PROGRAM UNIT FOR PRINTING CALCULATOR
Richard A. Edwards, Walnut Creek, and Charles A. Lindberg, Lafayette, Calif., Eugene E. Reynolds, Orangeburg, S.C., and James R. Wilson, Jr., Berkeley, Calif., assignors to SCM Corporation, New York, N.Y., a corporation of New York

Continuation of application Ser. No. 330,844, Dec. 16, 1963. This application Dec. 1, 1966, Ser. No. 596,202
8 Claims. (Cl. 235—60)

This application is a continuation of the U.S. patent application Ser. No. 330,844, filed Dec. 16, 1963.

The invention relates generally to a printing calculator having a pin carriage that is shiftable relative to a plurality of storage registers including an accumulator-product-dividend register, a multiplier register, and a counter register; more particularly the invention concerns improved calculation control mechanisms in combination with an integrated program unit under control of single and multifunction control keys, selective depression of which keys serves to: (1) initiate, under control of the program unit, a transfer of a multiplier value selectively from the accumulator register, the counter register, or the pin carriage, to the multiplier register in short-cut form and cause the value invariably to be printed as a multiplier value; (2) initiate, under control of the program unit, a short-cut multiplication operation carried out according to a selected multiplier value from higher to lower orders; and (3) initiate, under control of the program unit, a division operation during which additional lower orders of the storage registers are activated automatically to enable development in the counter register of a quotient that extends into the lower orders and is available thereafter for transfer to the multiplier register for use as a multiplier.

In presently available mechanical calculating machines certain problems arise. One such problem is the lack of ease with which the operation of the machine may be modified. In these machines, addition, subtraction, multiplication and division operations are selectively performed under control of several program mechanisms. These program mechanisms generally are designed to control an operation in a predetermined manner and only in that manner. Such program mechanisms are controlled, directly, by means of a control key for initiating a selected operation, usually requiring a heavy key depression. In some of these machines the mechanism for each program is separate from the mechanism for the other programs and each is designed specifically for control of one operation. In other machines the program mechanisms are interdependent to the extent that one program cannot be modified without affecting another program. Revision of either type of mechanism, even for a minor variation in program, is exceedingly difficult and would be so extensive as to make such revision unfeasible. For example, calculating machines are known which comprise a clutch for shifting, a clutch for actuation, various other clutches and control means specific to multiplication and several separate mechanisms for controlling each specific program. To alter one of the existing operations or add an additional one, as for example, to modify the machine to square a value upon depression of a single control key, would require substantial modification. One proposed modification for such a squaring operation would require the addition of an extra clutch, an extra cam, another key, the addition of mechanism associated with the added clutch, cam and key, and redesign of the existing mechanism in order to provide room for the added parts. In the present invention, a program unit is provided that has a plurality of function plates, one plate being provided

2

for each program. These plates may be easily removed and replaced by another plate for control of another program.

A second problem in presently available printing calculating machines is the inability to check and prove the results of calculations. In known printing calculators, a mechanism is provided for controlling the transfer of a multiplier value from one of a plurality of storage registers to the multiplier register or from value entry means to the multiplier register for use as a multiplier and thereafter as a stored multiplier. It is very desirable, after such a multiplier entry, to be able at a glance to check the source and value of the multiplier prior to initiating a subsequent multiplication operation, and at the conclusion of a multiplication operation to have the factors and product grouped together for checking. Such a feature is not generally available on known printing calculators. In the present invention, however, means are provided for printing each multiplier value, multiplicand value and product value, one under the other, for easy, convenient checking.

Another problem in presently available calculating machines is the low speed of operation during multiplication. It is desirable to arrange a calculating machine to operate as rapidly as possible during multiplication while minimizing the number and complexity of parts. One well known method of increasing the speed of a multiplication operation is to provide means for short-cut multiplication. Normally, however, such multiplication is carried out according to the lowest multiplier order and then successively to higher multiplier orders. In a calculating machine that also performs division, it is desirable to carry out multiplication according to the highest multiplier order and then to successively lower multiplier orders, i.e. in the same direction that division is carried out. In ten key machines, such an arrangement minimizes the number of parts required in that portions of the mechanism used to line up the factors during multiplication and division and portions of the mechanism used to end the operations need not be duplicated. Furthermore, in ten key machines that use a pin carriage shiftable with respect to the registers, the pin carriage is in the rightward position at the end of all operations, ready for immediate clearance.

Still another problem in ten key calculating machines is manipulation of the machine prior to a division operation, i.e. entry of factors to ensure that a quotient having a sufficient number of orders is developed. For example, in one well known machine, 4 divided by 7 produces no quotient whatsoever. To produce a significant quotient in such a problem the dividend must be entered at the keyboard and then zeros entered to move the dividend leftward. In certain other division problems where a product, sum, or difference is to be used as a dividend, the value must be re-entered to obtain a sufficient number of quotient orders or the operator must be satisfied with the number available. In the present invention, extended lower orders are provided in all registers, which orders are automatically activated during a division operation in order that a quotient is developed having at least the number of extended orders.

A printing calculator, according to the invention, comprises mechanism necessary for multiplication and division, which mechanism is combined with a basic adding machine structure found in currently produced Marchant 900 or 1100 model adding machines. The basic adding machine structure comprises ten value keys for entry of values into a pin carriage shiftable relative to a stationary accumulator register. Values in the pin carriage may be transferred to the accumulator register by means of ordinary reciprocating actuator rack assemblies. The adding machine structure also includes adding machine control

keys for initiating operations and accumulator register controls for raising, lowering, and centralizing the accumulator register with respect to the rack assemblies. The multiplication and division mechanism that is combined with the adding machine structure includes a multiplier register for temporary storage of multiplier values during multiplication problems. It also includes a counter register for registering quotient values and for permanent storage of multiplier values. A single tooth gear for counting out the multiplier value in the multiplier register during multiplication and for developing a quotient in the counter register during division is also provided and is shiftable with the pin carriage relative to the registers. Multiplier and counter register controls are provided for selectively raising the multiplier register and the counter register for engagement with the single tooth gear and lowering the register for engagement with the rack assemblies. A printing mechanism is also provided for printing all operands and results on a paper tape.

An integrated program unit is provided for control of the printing calculator during multiplication and division problems. This program unit is directly controlled by the multiplication and division control keys and comprises a plurality of program plates including control plates and function plates. A function plate is provided for each of the programs that the machine is to perform and is selected by depression of the appropriate control key, the arrangement being such as to require only a very light key depression. The control plates are operable during every program for starting the machine and for sensing a selected function plate during the program. Each of the function plates comprises a plurality of control surfaces at various levels for step by step control of the calculator according to the levels of the surfaces. Such a program unit is integrated, flexible and may be easily modified by removing a function plate then replacing the plate with another that has control surfaces at different levels. In such an arrangement it is also convenient to provide space for the addition of new function plates.

In order to provide a printing calculator that produces a record with results that may be easily checked and proved, means are provided to print all multipliers next to the corresponding multiplicand and result of each multiplication problem. A multiplier value is printed whenever a value is transferred to the multiplier register from the pin carriage, the accumulator register, or the counter register in response to depression of a multiplier entry key and appropriate natural conditioning. One such conditioning occurs whenever a value is entered into the pin carriage. This automatically conditions the machine to transfer the value in the pin carriage to the multiplier register upon depression of the multiplier entry key. Another such conditioning occurs when there is no value in the pin carriage. In this case the machine is automatically conditioned by the lack of a value in the pin carriage so that upon depression of the multiplier entry key, the value in the counter register is transferred to the multiplier register. A final conditioning occurs when a subtotal multiplication initiating key is depressed and latched down to initiate a subtotal equals multiplication operation. After such an operation, the value in the accumulator register may be transferred to the multiplier register upon depression of the multiplier entry key. In each of the above cases, the multiplier value is deliberately transferred to the multiplier register and the value is printed on the paper tape. After a multiplier entry cycle, a multiplicand is entered into the pin carriage and a multiplication operation is initiated by depression of an appropriate multiplication initiating key. During the ensuing multiplication operation, the multiplicand is printed and then the product is printed so that the multiplier, multiplicand, and product are printed one immediately under the other on the tape to provide a permanent, easily checked printed record of the problem.

During a multiplication operation following entry of a multiplicand value in the pin carriage, the pin carriage is escaped leftward against the highest one of a group of ordinal lineup stops which are set during a multiplier entry cycle. The lineup stops are set by sensing the rack assemblies during the multiplier entry cycle to detect all orders in which the multiplier value lies. If a short-cut carry emanates from the highest multiplier order a corresponding stop is set accordingly. The lineup stops are set during a division operation in a similar manner by sensing all orders of the rack assemblies to determine in which order the dividend value lies. The lineup stop associated with the order to the left of the highest order is then used to block leftward movement of the pin carriage during each of the operations. For multiplication, the entire lineup stop assembly is positioned to stop movement of the pin carriage so that the lowest multiplicand order aligned with the highest multiplier order. During division the entire lineup stop assembly is positioned to stop movement of the pin carriage with the highest divisor order aligned with the highest dividend order.

After the pin carriage is moved to a position for either a multiplication or division operation, a holding rack and a shifting rack are raised for holding and shifting the pin carriage relative to the registers. The pin carriage thereafter is ordinally shifted rightward by the shifting rack and held in ordinal positions by the holding rack until digitation is completed. Such shifting is entirely independent of any of the registers or of the lineup stops which are reset soon after the holding and shifting racks are raised for control of the pin carriage. During a multiplier entry cycle, short-cut stops are set according to the value transferred to the multiplier register and short-cut carries are registered by means of a tens carry mechanism associated with the rack assemblies. The short-cut stops are set independently of the multiplier register and are ordinally and cyclically sensed during a subsequent multiplication operation. Since the pin carriage is power shifted during multiplication operations, the pin carriage is also shifted independent of the short-cut stops. Such an arrangement, with a power shifting mechanism that is not actuated by multiplier register numeral wheels, lineup stops or short-cut stops, leaves all of the mechanism lightly loaded, thus minimizing the wear and strain on all of the parts.

In all of the registers, additional lower orders are provided that are not normally used during multiplication and are never used during addition and subtraction. These orders are automatically activated upon depression of the divide key for use during division operations. Dividend values may be entered only in the normal orders of the accumulator register, the lower orders being provided to enable quotient values to be developed that extend into the additional lower orders. Such an arrangement permits products, sums, and differences, large and small, to be used as dividends, without re-entering the values in higher orders of the accumulator register. Thus, with such dividend values a quotient value may be obtained that is assured of having a reasonable number of significant orders; and in the case where a dividend is entered into the higher orders of the accumulator register, in the conventional manner, a quotient value is obtained that has significant orders of a greater number than obtained in known ten key machines.

Following a division operation, the quotient value remains in the counter register as a stored multiplier, available for transfer, including the additional lower orders, to the multiplier register for use in a multiplication operation. During such an operation, the multiplicand is accumulated in the normal orders of the accumulator register according to the full multiplier value. During entry of a multiplicand value by means of value keys, whether the previously entered multiplier value lies only in normal orders of the multiplier register or extends into the additional lower orders, keyboard overcapacity

controls are provided to block the value keys from further entry to prevent development during a multiplication operation of a product that exceeds the capacity of the product register.

An object of the invention is to provide an improved calculating machine.

Another object is to provide an improved printing calculator.

Another object is to provide an integrated program unit from which a program may be selected by depression of a control key and the program carried out thereafter under control of the program unit.

Another object is to provide a flexible program unit in which programs may be modified, deleted and added.

Another object is to include a plurality of function plates in a program unit, each of which plates may be used to control the machine to carry out a particular program.

Another object is to provide a program unit with function plates having surfaces for control of the machine, corresponding surfaces on each of the plates being sensed by a common sensing means.

Another object of the invention is to provide a mechanical program unit with a function plate having a plurality of surfaces for control of the machine and which may control the machine according to a first surface during a program and then according to a second surface and then later in the program to control the machine again according to the first surface.

Another object is to produce a printed record of all calculations, which record is convenient to prove and check.

Another object is to provide a printing calculator that invariably prints each multiplier value immediately adjacent to the other factors of a multiplication problem for convenience in proving and checking the results and for use as a permanent record.

Another object is to provide a printing calculator in which depression of a multiplier entry key is invariably required to enter a multiplier value into a multiplier register.

Another object is to provide a calculating machine in which a multiplier value may be transferred from one of three locations to the multiplier register.

Another object is to provide a calculating machine which is automatically conditioned to transfer a multiplier value from a selected one of three locations to the multiplier register upon depression of the multiplier entry key.

Another object is to provide a high-speed calculating machine that has a minimum number of parts and that operates with a minimum of wear and strain on the parts.

Another object is to carry out short-cut multiplication according to a multiplier value from higher to lower orders without requiring the numeral wheels to drive other mechanisms.

Another object is to provide a common lineup mechanism that is operable to line up the factors during both multiplication and division.

Another object is to arrange a calculating machine with a maximum number of mechanisms that are in common usage in division and during multiplication operations to thereby diminish the total number of parts required.

Another object is to set ordinal lineup stops to control lineup of the factors during both division and multiplication, and during multiplication to set the stops according to any short-cut carry into the highest order.

Another object is to power-shift the pin carriage independently of any registers during both division and multiplication.

Another object is to automatically condition a calculating machine upon initiation of a subtotal multiplication operation to transfer the product of such a multiplication to the multiplier register upon subsequent depression of the multiplier entry key.

Another object is to automatically extend, upon depression of a divide key, the capacity of a quotient register.

Another object is to provide a calculating machine that may use an extended quotient value as a subsequent multiplier value and to generate a product in the unextended orders of a product register.

Another object is to provide a calculating machine that may repeatedly use an extended quotient as a multiplier value.

Another object is to prevent entry of a multiplicand value into the pin carriage that would result in a product exceeding the capacity of the product register, whether the multiplier value lies entirely in the normal orders of the multiplier register or whether the multiplier value extends from the normal orders into the additional lower orders.

Another object is to provide a holding rack and a shifting rack, operable during division and multiplication operations, to control the position of the pin carriage.

Another object is to provide a short-cut mechanism in which the sensing means operate independently of the numeral wheels of the multiplier register.

Another object is to provide ordinal short-cut stops that are reset to normal positions during the multiplication operation by power means independent of the multiplier register numeral wheels.

Another object is to provide a short-cut mechanism in which a zero sensing mechanism performs the dual function of sensing the numeral wheel for zero and upon sensing a zero, resetting the ordinal short-cut stop in the order in which the sensing occurred.

Another object is to provide a tens carry mechanism which has the dual function of registering tens carries and short-cut carries.

Another object is to provide a short-cut multiplication mechanism in which the first cycle of the mechanism is controlled solely by the program unit and not according to the setting of the highest order short-cut stop.

Another object is to use a piece of stock metal for use as a minus symbol for printing.

Another object is to clear the pin carriage by means of a movable clear plate, which plate is movable simultaneously with the pin carriage.

Another object is to integrate rollback, spacing and dipping mechanism for positive continuous control of the platen during a printing operation.

Other objects and advantages will appear from the following description, given by way of example only, in which:

FIG. 1 is a top plan view of a calculating machine embodying the present invention;

FIG. 2 is a functional diagram of a printing calculator showing the main components of the calculator in block form;

FIG. 3 is a right side view in section showing a portion of the value entry mechanism, an accumulator register, a multiplier register, a counter register, ordinal reciprocating actuator rack assemblies for actuating the numeral wheels of the registers, portions of a printing mechanism, and zero suppression mechanism;

FIG. 3A is a right side view showing additional parts of the zero suppression mechanism;

FIG. 3B is a front view of part of the zero suppression mechanism;

FIG. 4 is a right side view of a mechanism for driving the ordinal reciprocating actuator rack assembly;

FIG. 5 is a timing diagram pertaining to movement of the ordinal reciprocating actuator rack assemblies and portions of the mechanism involved in printing operations;

FIG. 6 is a top view of trip slides underlying adding machine control keys;

FIG. 7 is right side view of the trip slides shown with portions of the adding machine keys and a starting bail;

FIG. 8 is a right side view of a main clutch and associated mechanism;

FIG. 9 is a right side view of control slides, followers, a vertical slide and associated mechanism for raising, lowering, and centralizing the accumulator register with respect to the rack assemblies;

FIG. 10 is a front view showing the relationship of the trip slides to the starting bail and a keyboard sensing slide for control of the control slides;

FIG. 11 is a front view of the starting bail showing associated mechanism actuated thereby;

FIG. 12 is a right side view of a starting mechanism for engaging the main clutch;

FIG. 13 is a front view of a blocking lever for blocking the control slides and shows associated mechanism for printing control during adding machine functions;

FIG. 13A is a right side view of portions of the printing control mechanism;

FIG. 14 is a right side view of cams that actuate the followers of FIG. 9;

FIG. 14A is a top view of the cams of FIG. 14;

FIG. 15 is a top view of the followers of FIG. 9;

FIG. 16 is a front view of a portion of the vertical slide of FIG. 9 shown in all significant positions;

FIG. 17 is a timing diagram pertaining to the operation of the accumulator register during various cycles and the operation of a pin carriage clearance mechanism;

FIG. 18 is a perspective view taken from the right hand side showing portions of the accumulator register and associated controls therefor;

FIG. 49A is a top view of a portion of the program drive link and associated mechanism;

FIG. 49B is a top view of another portion of the program drive link and associated mechanism;

FIG. 50 is a top view of a square plate of the program unit;

FIG. 51 is a right side view of a powered sensing slide for control of the multiplier and counter registers;

FIG. 51A is a right side view of a driving mechanism for the powered sensing slide;

FIG. 52 is a right side view of an early slide for control of the multiplier and counter registers;

FIG. 52A is a right side view of mechanism for driving the early slide;

FIG. 53 is a right side view of a late slide for control of the multiplier and counter registers;

FIG. 53A is a right side view of a mechanism for driving the late slide;

FIG. 54 is a timing diagram of the operation of the powered sensing slide, the early slide, and the late slide, and various other mechanisms of the invention;

FIG. 55 is a right side view of mechanism for raising, lowering, and centralizing the multiplier register and counter register;

FIG. 55A is a right side view of a lineup stop and related mechanism;

FIG. 56 is a right side view of division overdraft controls;

FIG. 56A is a right side view of additional division overdraft controls;

FIG. 56B is a front view of a portion of the mechanism 75 of FIG. 56A;

FIG. 57 is a right side view of a counter register clearing mechanism;

FIG. 57A is a top view of a portion of the counter register clearing mechanism;

FIG. 57B is a front view of a portion of the counter register;

FIG. 58 is a right side view of a mechanism for driving and controlling the setting of the lineup stops;

FIG. 58A is a right side view of related mechanism for controlling the setting of the lineup stops;

FIG. 59 is a right side view of mechanism for controlling the rotation of the single tooth gear;

FIG. 59A is an enlarged section of FIG. 59 taken along lines 59A—59A showing additional mechanism for driving and controlling the single tooth gear;

FIG. 60 is a top view of a countout carriage, a shifting rack, a holding rack, a portion of the pin carriage and related mechanism;

FIG. 60A is a front view of a comb extending from the pin carriage;

FIG. 61 is a right side view of mechanism for latching the countout carriage to the pin carriage;

FIG. 62 is a right side view of countout carriage home order controls and of a shifting rack and a holding rack and associated mechanisms;

FIG. 62A is a top view of a portion of the home order controls of FIG. 62;

FIG. 62B is a front view of the shifting rack and the holding rack and a portion of the driving mechanism;

FIG. 63 is a right side view of a short-cut stop setting, sensing and restore mechanism;

FIG. 64 is a right side view of a zero sensing and short-cut sensing driving mechanism;

FIG. 64A is a top view of a portion of the short-cut sensing mechanism;

FIG. 65 is a top view of portions of the zero and short-cut sensing mechanism;

FIG. 65A is a right side view of a mechanism connecting the short-cut sensing mechanism to program plate control mechanism;

FIG. 66 is a right side view of a mechanism for controlling, shifting and clearing of the pin carriage;

FIG. 67 is a right side view of a four lower order latch and related mechanism for automatically activating additional lower orders in the registers and rack assemblies.

FIG. 68 is a right side view of various home order latching mechanisms;

FIG. 69 is a right side view of a zero gear for control of the program unit;

FIG. 70 is a front view of the four order latch;

FIG. 71 is a right side view of a portion of the keyboard overcapacity controls;

FIG. 72 is a front view of the mechanism of FIG. 71 and related mechanism of the keyboard overcapacity controls;

FIG. 73 is a right side view of a portion of the keyboard overcapacity controls and a lineup stop;

FIG. 74 is a right side view of an alternate embodiment of a portion of the keyboard overcapacity controls.

GENERAL DESCRIPTION

The invention may be discussed generally by reference to a calculating machine 100 (FIG. 1) drawn to a reduced scale, a simplified schematic diagram of the machine shown in FIG. 2, and portions of internal structure of the machine shown in FIG. 3. The machine 100, in which the invention is embodied, is motor driven and is cyclically operable under control of various control keys and a keyboard comprising ten value keys 101 (FIG. 1). The control keys may be divided into two groups: first, adding machine control keys 201 (FIG. 2) including an add-total key 103 (FIG. 1), a repeat add key 104, a subtotal-correction key 105, a minus key 107, and a nonadd key 109; and second, multiplication-division control keys 203

(FIG. 2), including a multiplier entry key 110 (FIG. 1), a total = key 112, a subtotal = 114, a negative = key 116, and a divide key 118. Other keys include a space lever 119, a dividend tab key 120, and a tab stop lever 122.

The machine, in general, comprises digital actuators in the form of ordinal reciprocating actuator rack assemblies generally indicated at 300 (FIG. 3) and omitted from FIG. 2 for purposes of clarity. Each assembly 300 comprises a main member 301 and a register drive rack 303 carried thereby. The assemblies are differentially operable under control of a value entry mechanism comprising a pin carriage generally indicated at 205 (FIGS. 2 and 3) and value keys 101. Values are entered into the pin carriage in a serial manner by successive depression of selected ones of the value keys 101. Such depression detents a corresponding pin 304 to a position 304-A into the path of a shoulder 305 extending from a rack assembly 300. The rack assemblies, under control of the pin carriage, serve to drive corresponding ordinal numeral wheels 306 (FIG. 3) of an accumulator register 207 (FIGS. 2 and 3) as well as numeral wheels 307 and 309 of a multiplier register 209 and a counter register 211, respectively. The rack assemblies 300 also releasably drive corresponding ordinal printing segments 311 to the value represented in the racks in the manner disclosed in co-pending U.S. application Ser. No. 103,346 to Richard A. Edwards, since matured into Patent No. 3,142,441, issued July 28, 1964.

Briefly, in response to depression of certain control keys, the numeral wheels 306, 307 and 309 are carried selectively upwards or downwards on respective supporting shafts 310, 312, and 313. The numeral wheels are carried thereby into and out of engagement with teeth on the register drive rack to be driven by the racks to value representing positions, the racks being selectively under control of the accumulator register 207, the counter register 211 or the pin carriage 205 in a manner fully discussed hereinafter.

Specifically, as disclosed in the above-mentioned Edwards application, the mechanism for driving the ordinal printing segments 311 (FIG. 3) includes the main member 301 which has a notch 315 cut in an upper extension thereof. An ear 316, carried by a releasable connecting member 318, normally lies within the notch 315. The member 318 is pivoted at 319 to a supplementary printing segment driving element 321 and is urged CW by a spring 322, thus connecting the element 321 to the member 301 for movement of the member and the element as a unit. The printing segment 311 is mounted freely on a transverse shaft 324, and has gear teeth 325 which are driven by element 321.

A transverse rod 326 is carried by a cam plate 375 (FIG. 3A) from the full position shown to a position 326-A in a manner described in the Edwards application, releasing the printing segments 311 to be driven to the printing positions. The rod 326 is subsequently carried CW, driving all of the segments 311 to the initial positions. A selected value, as represented by selectively advanced positions of segments 311, is printed by moving a platen 327 towards the left to press a paper tape 328 and a ribbon 329 against one of ten type faces 323 on the printing segment 311.

The rack assemblies 300 and printing segments 311 are driven every machine cycle; for example, depression of a control key, such as the add-total key 103, initiates a single cycle of rotation of a main operating shaft 330. A pair of complementary drive cams 400 and 401 (FIG. 4) are keyed to a right portion of the shaft 330. A similar pair of cams (not shown) are keyed to a left portion of the shaft 330. All of the cams 400 and 401 are rotated CCW with the shaft 330. A pair of rollers 402 and 403 are mounted on a follower lever 404 to follow the cams 400 and 401 respectively, and to rock the lever 404 about a shaft 405. Also mounted on the shaft 405 is a

forked lever 406 connected by an adjustable fastener 407 to the lever 404 for movement therewith. The movement of lever 406 in response to 360° of rotation of cams 400 and 401 is diagrammatically illustrated in line 5A of FIG. 5. The forked lever 406 is engaged with a transverse cyclically operable actuator drive means comprising a shaft 408 (FIGS. 3 and 4) guided in appropriate slots (not shown) in the framework of the machine for reciprocation of the shaft 408 between an initial leftmost position, and a driven rightmost position 408-A.

In the initial leftmost position, the actuator drive shaft 408 is in engagement with a notch 331 in a driving lever 332. The lever 332 is freely mounted on a pin 333 on the main member 301 and is urged CCW by a spring 334 to engage the shaft 408. During rotation of the complementary cams 400 and 401, the actuator drive shaft 408 is moved rightward by the forked lever 406. At such time the lever 332, the rack assembly 300 including the printing segment 311 and the driving element 321 are carried to the right as a unit until blocked, as for example, by the shoulder 305 being against a selectively ejected pin 304 standing in the path of the shoulder. When the rack assembly 300 and the lever 332 are blocked from further rightward movement, the continuing rightward movement of the drive shaft 408 carries the shaft out of the notch 331. This rotates the lever 332 CW, driving a locking ear 336 on lever 332 into engagement with a toothed rack 337 which is fixed to the framework of the machine. The rack assembly 300 is firmly held thereby in a selectively driven position while the drive shaft 408 is driven to an extreme rightward driven position. The shaft 408 is fully rightward near the end of the first 180° of rotation of shaft 330, as indicated on line 5A of FIG. 5.

The above described CW movement of lever 332 moves a restraining means in the form of an ear 338 into the path of a shoulder 339 on the printing segment drive element 321, thus preventing further movement of element 321 and printing segment 311 in response to inertial forces.

During the above-mentioned rightward movement of the main member 301, a side 340 of the notch 315 abuts the ear 316 and moves the member 321 thus driving the printing segment 311 CCW to the printing position which corresponds to the position to which the member 301 is driven. At the end of the rightward stroke of the actuator drive shaft 408, a cam driven holding means such as locking bail 341, fully described in the Edwards application, is automatically brought into engagement with locking teeth 342 to maintain the printing segment in the printing position. The motion of the cam which drives the locking bail 341 is indicated on line 5B of FIG. 5. During the second 180° of rotation of the main shaft 330, the cams 400 and 401 drive the lever 406 leftward to the initial position and the shaft 408 leftward into engagement with the notch 331. Upon such re-engagement, the lever 332 is rocked CCW by spring 334 so that the ear 336 moves out of engagement with the toothed rack 337. This unlocks the assembly 300 from the rack 337 to permit the shaft 408 to return the assembly leftward to the initial position.

Since, as indicated on line 5B, the printing segments 311 are maintained in a locked position by the locking bail 341 during leftward movement of the assembly 300, camming surface 315 engages and rocks the ear 316 upward, disconnecting the element 321 from the main member 301. The main member 301 and the register drive rack 303 are therefore driven leftward to the initial positions while the element 321 and the printing segment 311 are maintained locked in the printing position. During this period, as indicated on line 5C of FIG. 5, the platen 327 is cam driven CCW forcing the tape 328 and the inked ribbon 329 against one of the type faces of the printing segment 311 to print a character on the

tape corresponding to the rotated position of the printing segment. As further indicated on line 5C, the platen is returned to the initial position at the end of the printing operation, the bail 341 is rocked out of engagement with the locking teeth 342, and the rod 326 is returned to the initial position, thereby returning the printing segments 311 to respective initial CW positions. Clockwise driving of the printing segment 311 by the rod 326 acts through the gear teeth 325 to force the element 321 leftward. As indicated on lines 5A and 5B, the main members 301 are restored to the initial position before the printing segment 311 and the element 321 are restored. The ear 316 engages a camming surface 344 during leftward movement of the element 321, rocking the connecting member 318 CCW to permit the ear 316 to re-engage the notch 315 and re-establish the drive connection between the member 301 and the element 321.

Basically, in addition to the structure described above, the machine 100 (FIG. 1) comprises the units shown in the schematic diagram of FIG. 2, information flow between the units being indicated by solid arrows and control functions by dotted arrows. The diagram includes the accumulator register 207 in which values represented in the pin carriage 205 may be added into and subtracted therefrom, such entry being carried out by means of the racks 303 (FIG. 3), and the direction of information flow being indicated by an arrow 213.

Values entered into the accumulator register are printed on the tape 328 by a printing mechanism 214 including the segments 311, the platen 327 and the ribbon 329 as well as other mechanism discussed hereinafter. The direction of such information flow is indicated by an arrow 223.

The multiplier register 209 is provided to receive multiplier values in short-cut form and the counter register 211 is provided to receive multiplier values in true form, multiplier values being entered invariably into both registers simultaneously. Transfer of multiplier values into the registers 209 and 211 may be from the pin carriage 205 indicated by the arrows 215 and 217, or the accumulator register 207, indicated by the arrows 219 and 221. A short-cut multiplier value entered into the register 209 may be used to develop a product and is cleared from the register 209 during the development. The corresponding true multiplier value, however, remains in the counter register 211 at the end of a multiplication operation, available for transfer to the multiplier register 209 in short-cut form to carry out a second multiplication operation using the same multiplier. Since the multiplier values are stored in true form in the counter register, the value in true form may be printed on the tape 328 when transferred to the multiplier register, transfer to the multiplier register 209 and the printing mechanism 214 being indicated by arrows 223 and 225. The counter register 211, in addition to storing constant multipliers, is the register in which quotient values are developed during division.

Accumulator register controls 227, under selective control of the adding machine control keys 201 or a program unit 229, are provided to carry the accumulator register 207 into and out of engagement with the racks 303 at appropriate times called for by the operation. Similarly, multiplier and counter register controls 231, primarily under control of the program unit 229, are provided to carry the multiplier and counter registers 209 and 211 to the centralized positions indicated in FIG. 3, downward into engagement with the racks 303 or upward into engagement with a single tooth gear 346, the gear 346 being more fully discussed hereinafter. The program unit 229 is under control of the multiplication-division control keys 203, and upon depression of one of the keys 203, control of the machine 100 is entirely transferred to the program unit 229. For example, the accumulator register controls 227 and the multiplier and counter register controls 231, under control of the program unit 229 selectively position the register 207, 209, and 211 to carry out multiplication,

division, and printing operations and transfer of values between registers 207, 209, and 211.

More specifically, the functions of the invention in carrying out addition, subtraction, multiplication and division are related to depression of individual control keys and can be discussed by reference to FIGS. 1, 2, and 3, other specific structure of the machine 100 to carry out the functions being discussed later.

Add-total key

The add-total key 103 is a dual function key, depression of which causes either an add cycle or a total cycle depending on whether or not a value is represented in the pin carriage 205. With a value in the pin carriage, depression of the add-total key initiates an add cycle during which a value in the pin carriage 205 is added into the accumulator register 207 and printed in black on the tape 328; and with no value in the pin carriage, depression of the add-total key 103 initiates a total cycle during which the value in the accumulator register 207 is printed in red on the tape 328 and cleared from the register.

Add-total key, add function.—Prior to initiation of an add cycle, an augend is entered into the pin carriage 205 by depression of the value keys 101, highest order first, to eject underlying pins 304. Depression of the add-total key 103, with a value in the pin carriage 205, initiates a machine cycle during which the rack assemblies 300 are driven rightward and the printing segments 311 CCW to a position in which the assemblies and segments are blocked by the ejected pins, the augend being thereby transferred to the racks and segments. While the racks 303 are in the rightward position, the accumulator register 207, under control of the accumulator register controls 227, is carried upward into engagement with upper rack teeth 348 in order that the racks drive the numeral wheels 306 CCW during the leftward stroke, thereby transferring the augend from the racks to the register. After the segments 311 have been positioned they are disconnected from the racks 303 and the platen 327 is urged against the tape 328, ribbon 329 and segments to print the augend value in black. The accumulator register 207 remains in engagement with the rack teeth 348 at the end of the cycle and is disengaged at the beginning of the next cycle.

Referring to FIG. 2, the transfer of values in the pin carriage 205 to the accumulator register 207 is indicated by the arrow 213, and printing of the values at the printing mechanism 214 by the arrow 233. Near the end of the cycle, the detented pins 304 are restored, thereby clearing the pin carriage 205. Further depression of the value keys 101 enters an addend into the pin carriage and a second depression of the add-total key 103 transfers the addend additively into the accumulator register 207 in the manner discussed. Subsequent addends may be entered and transferred to the register 207 to the limit of its capacity. Each value transferred to the accumulator register under control of the add-total key is printed in black on the tape 329.

Add-total key, total function.—The second function carried out by depression of the add-total key 103 is totaling. Depression of the add-total key 103 without a value in the pin carriage 205 initiates a debit total cycle during which a total debit value in the accumulator register 207 is cleared from the register and printed in red on the tape 328 followed by the symbol T. At the beginning of a debit total cycle, prior to a rightward stroke of the racks 303, the accumulator register 207, under control of the accumulator register controls 227, is carried upward into engagement with upper rack teeth 348, permitting the numeral wheels 306 to be driven CW to zero during the rightward stroke of the racks. The numeral wheels 306 are blocked at zero, by means hereinafter discussed, from further rotation and thereby block the racks 303 and printing segments 311 in positions representing the total debit value from the accumulator

register 207. The accumulator register 207 under control of the controls 227, is disengaged from the teeth 348 and centralized before the leftward stroke of the racks. During a debit total cycle therefore, a total debit value in the accumulator register 207 is transferred to the racks 303 and printing segments 311, the register 207 being zeroized during the transfer. The printing segments 311, under control of the printing mechanism 214, print the total debit value in red on the tape 328 followed by the symbol T.

If the value in the accumulator register 207 is a total credit, depression of the add-total key 103 initiates a credit total cycle during which the register 207 is driven downward into engagement with lower rack teeth 350, the numeral wheels 306 are driven CCW to zero during the rightward stroke of the racks thereby clearing the register 207 and blocking the racks 303 and segments 311 in positions representing the total credit value, and printing the total credit value represented by the segments in red followed by a T-symbol.

Repeat add key

The repeat add key 104 serves the same purpose as the add-total key 103 when functioning as an add key, an add cycle being initiated upon depression thereof, except that the pin carriage 205 is prevented from clearance at the end of the cycle. A value in the pin carriage 205 can therefore be repeatedly added into the accumulator register 207 without re-entering the value into the pin carriage. Depression of the repeat add key 104 without a value in the pin carriage initiates a cycle during which the paper tape 328 is fed without values or symbols being printed.

Subtotal-correction key

The subtotal correction key 105 is a dual function key similar to the add-total key 103, and likewise which of the two functions that is carried out in response to depression thereof, is determined by the position of the pin carriage 205, i.e. whether the pin carriage is clear or represents a value. Without a value in the pin carriage 205, a subtotal cycle is carried out and with a value in the pin carriage, a correction cycle is carried out.

Subtotal-correction key, subtotal function.—Depression of the subtotal correction key 105 without a value in the pin carriage 205 and with a debit value in the accumulator register 207, initiates a debit subtotal cycle during which the debit value is printed in red on the tape 328 followed by the symbol S. At the beginning of a debit subtotal cycle, the accumulator register 207, under control of the accumulator register controls 227, is carried upward into engagement with the rack teeth 348, remaining in engagement during both the rightward and leftward strokes of the racks. During the rightward stroke, the numeral wheels 306, when zeroized, block the racks 303 and printing segments 311 from further movement. The debit value is therefore transferred from the accumulator register 207 to the printing segments by the racks 303 for printing under control of the printing mechanism 214. Since the register 207 remains in engagement with the teeth 348, the value is re-entered into the register 207 during the leftward stroke of the racks.

If the value in the accumulator register 207 is a credit, depression of the subtotal-correction key 105 initiates a credit subtotal cycle during which the register 207 is carried downward into engagement with the rack teeth 350 and the value, followed by the symbol S—, printed in red on the tape 328.

Subtotal-correction key, correction function.—Depression of the subtotal-correction key 105 with a value in the pin carriage 205, initiates a correction cycle during which the only function carried out is clearance of the pin carriage 205; otherwise, all registers are maintained in normal positions, out of engagement with the racks, and the platen is not rocked against the tape, ribbon, and printing segments.

Depression of the minus key 107 (FIG. 1) initiates a minus cycle during which a value in the pin carriage 205 is subtracted from the accumulator register 207 and printed in black on the tape 328 followed by a — symbol. During a minus cycle, the racks 303 are driven rightward and the printing segments 311 CCW to a position in which the racks are blocked by ejected pins 304 representing the value, the value being thereby transferred to the racks and printing segments. Before the leftward stroke of the racks, the accumulator register 207, under control of the accumulator register controls 227, is carried downward into engagement with the lower rack teeth 350 in order to drive the numeral wheels 306 CW during the stroke, subtracting the value in the racks from the register 207. The printing segments 311 are disconnected from the racks 303. The platen 327, under control of the printing mechanism 214, is urged against the tape 328 after the segments are positioned to print the value in black followed by a — symbol.

Nonadd key

The nonadd key 109 is a dual function key, similar to control keys previously discussed, provided to initiate a nonadd cycle upon depression thereof with a value in the pin carriage and upon depression of the key without a value in the pin carriage to initiate a multiplier readout cycle.

Nonadd key, nonadd function.—Depression of the nonadd key 109 with a value in the pin carriage 205 initiates a nonadd cycle during which the value is printed on the tape 328 in black followed by a nonadd symbol #. Transfer of the value in the pin carriage to the printing mechanism 214 is indicated by the arrow 235 in FIG. 2. All registers are maintained out of engagement with the racks 303 during a nonadd cycle, preventing entry of the value into any register.

Nonadd key, multiplier readout function.—With no value in the pin carriage 205, the multiplier and counter register controls 231 (FIG. 2) are under control of the nonadd key 109. Depression of the nonadd key 109 under these conditions initiates a multiplier readout cycle during which a stored multiplier value in the counter register 211 is printed on the tape 328 without clearing the register 211. During such a cycle, the counter register 211 under control of the multiplier and counter register controls 231, is carried downward into engagement with rack teeth 352 and is maintained in engagement throughout the cycle, the numeral wheels 309 being driven CCW to zero, blocking the racks 303 and the printing segments 311 in positions representative of the value. During the leftward stroke of the rack 303, the printing segments 311 are disconnected from the racks to print the multiplier value in black on the tape 328 followed by the symbol #; and at the same time, the numeral wheels 309 are driven CW by the racks during the leftward stroke, restoring the multiplier value to the register 211.

Dividend tab key and tab stop lever

Since depression of the add-total key 103 initiates transfer of a value in the pin carriage 205 to the accumulator register 207, the key 103 may be used to enter dividends into the accumulator register in a like manner. Upon entry of a value into the pin carriage 205 the carriage is normally escaped leftward one order for each digit entered; however, to obtain a larger number of digits in a quotient, it is necessary to escape the carriage 205 further leftward to position the carriage in one of two positions opposite higher accumulator register orders. After such escapement the add-total key 103 is depressed to enter the value into these orders. The dividend tab key 120 is provided for escaping the carriage to these orders.

Depression of the tab key 120 releases the pin carriage 205 to be spring urged leftward until blocked from further movement. The tab stop lever 122 is provided to

control blocking of the pin carriage 205 in either a partial tab position or a full tab position after depression of the tab key 120. With the lever 122 in the rightward position the pin carriage 205 is stopped in the partial tab position; and with the lever in the leftward position, the pin carriage is free to escape fully leftward to line up the highest pin carriage order with the highest order of the accumulator register 207.

Divide key

The divide key 118 is provided to initiate division operations. After entry of a dividend into the accumulator register 207 and a divisor into the pin carriage 205, depression of the divide key 118 actuates the program unit 229 to successively control the machine 100 to carry out a multicyclic division operation which includes: carrying out a nonadd cycle during which the divisor value is printed in black on the tape 328 followed by the symbol ÷; connecting the single tooth gear 346 to the pin carriage 205 opposite the lowest divisor order; automatically releasing the pin carriage 205 and single tooth gear 346 to be spring urged leftward to lineup the highest divisor order in the pin carriage with the highest dividend order in the accumulator register 207; clearing the counter register 211; raising the counter register 211, under control of the multiplier and counter register controls 231, into engagement with the single tooth gear 346; carrying out successive subtractions of the divisor in the pin carriage 205 from the dividend in the accumulator register 207 until an overdraft occurs; rotating the single tooth gear 346 one revolution during each subtraction, thereby entering one count for each subtraction into the counter register 211 with which the single tooth gear is engaged; sensing the overdraft; adding the divisor back once into the accumulator register 207; correcting the count in the counter register 211 by rotating the single tooth gear 346 once in the opposite direction; shifting the pin carriage 205 and the single tooth gear 346 to line up with the next lower order in the accumulator register 207 and counter register 209; subtracting again until overdraft; counting the subtractions; sensing the overdraft; adding back; correcting the count; shifting to the next lower order; and carrying out similar cycles in successive lower orders until the pin carriage is in a rightward "home" position. In order to develop larger and more useful quotients without re-entering dividends such as done in conventional machines, four extra lower orders are provided in the accumulator and counter registers 207 and 211, for use during division operations, the orders being suppressed at other times, except as hereinafter discussed.

During division, the pin carriage 205 is shifted through these orders so that at the end of division, the lowest order of the divisor value in the pin carriage is lined up with the lowest order in the accumulator register. The division operation is concluded with cycles during which the quotient value, i.e. the value developed in the counter register 211, is printed automatically on the tape 328 in red followed by the symbol Q; and printed in red below that, the remainder, i.e. the value remaining in the accumulator register, followed by the letters RM.

Multiplier entry key

The multiplier entry key 110 is a multifunction control key provided to initiate transfer of a multiplier value from one to three storage locations in the machine 100 to the multiplier and counter registers 209 and 211, the storage locations being the pin carriage 205, the counter register 211 and the accumulator register 207. The multiplier entry key 110 is invariably latched down when depressed and is released only by depression of the total = key 112, the subtotal = key 114, or the negative = key 116, depression of the = keys being ineffective unless the multiplier entry key 110 is first depressed and latched down.

Multiplier entry from pin carriage.—Depression of the multiplier entry key 110 with a value in the pin carriage

205 actuates the program unit 229 to control the machine 100 to carry out a keyboard $\times_{KB}$ multiplier entry cycle during which the value in the pin carriage is transferred to the multiplier register 209 and the counter register 211 and is printed on the tape 328 in black followed by the symbol $\times$, such transfer being indicated by the arrows 215 and 217. During such a cycle, the racks 303 are driven to a rightward position under control of the pin carriage. The multiplier and counter register controls 231, under control of the program unit 229, carry the multiplier and counter registers 209 and 211 downward into engagement with the racks 303 prior to the leftward stroke of the racks, the value in the racks being transferred to the multiplier register 209 and the counter register 211 during the leftward stroke.

Multiplier entry from counter register.—Depression of the multiplier entry key 110 without a value in the pin carriage 205 actuates the program unit 229 to initiate and control a counter register multiplier entry cycle $\times_c$ during which a true value in the counter register 211 is transferred to the multiplier register 209 in short-cut form without clearing the counter register 211, the value being printed in black on the tape 328 followed by the symbol $\times$, with such transfer and printing indicated by the arrows 223 and 225 (FIG. 2). The multiplier and counter register controls 231, under control of the program unit 229 maintain the counter register 211 in engagement with the teeth 352 during the rightward and leftward strokes of the racks, and the multiplier register 209 in engagement with the teeth 352 only during the leftward stroke. The racks 303, during the rightward stroke, drive the counter register numeral wheels 309 to zero, the wheels blocking further rightward movement of the racks when zeroized. Prior to the leftward stroke, the multiplier register 209 is brought into engagement with the teeth 352 so that numeral wheels 307 and 309 of both registers are driven to the multiplier value during the stroke.

Multiplier entry from accumulator register.—With no value in the pin carriage 205, depression of the multiplier entry key 110, either simultaneously with or subsequent to depression of the subtotal = key 114, actuates the program unit 229 to initiate an accumulator register multiplier entry cycle $\times_A$ during which the value in the accumulator register 207 is transferred to the counter register 211 in the true form and to the multiplier register 209 in short-cut form, the value being cleared from the accumulator register and printed in red on the tape 328 followed by the symbol $\times$. The paths of information flow from the accumulator register 207 to the multiplier and counter registers 209 and 211 are indicated in FIG. 2 by the arrows 219 and 221. The accumulator register controls 227 and the multiplier and counter register controls 231, under control of the program unit 229, maintain the accumulator register 207 in engagement with the racks 303 only during the rightward stroke, and the multiplier and counter register 209 and 211 in engagement only during the leftward stroke. The accumulator register numeral wheels 306 are driven to zero during the rightward stroke, blocking the racks 303 from further movement when zeroized. Prior to the leftward stroke, the accumulator register 207 is taken out of engagement with the racks 303 and the multiplier and counter registers 209 and 211 are carried into engagement with the racks 303 and are driven to the multiplier value during the leftward stroke.

Total = key

The total = key 112 (T=) is provided for initiating a total = multiplication operation which is a multicyclic short-cut multiplication operation. During such an operation, the product is developed in the accumulator register 207, cleared from the register 207, and then printed in red on the tape 328 followed by the symbol T. After entry of a multiplier into the multiplier register 209 from

one of the three storage locations discussed, and entry of a multiplicand into the pin carriage 205, depression of the T= key 112 actuates the program unit 229 to initiate a multiplication operation during which the multiplicand value is printed in black on the tape 328 followed by the symbol =, the pin carriage 205 and a single tooth gear 346 are connected together and released to be sprung urged leftward to a position in which the lowest order of the multiplicand in the pin carriage 205 and the single tooth gear 346 lineup with the highest order of the multiplier value in the register 209. After lineup, the multiplier register 209 is carried upward for engagement with the single tooth gear 346. Then, multicyclic digitation operations, under control of the program unit 229, are automatically carried out, during which operations the multiplicand value in the pin carriage 205 is successively accumulated or added into the accumulator register 207 a number of times equal to the highest order value in the multiplier register. At the same time, the highest order numeral wheel 307 in the multiplier register 209, which is in engagement with the single tooth gear 346, is counted down to zero one count at a time by a single rotation of the single tooth gear 346 each cycle. Upon reaching zero, the condition of this order is sensed and the pin carriage 205 and single tooth gear 346 automatically shifted to line up with the next lower order of the multiplier register 209, after which, successive accumulations and countdown or successive subtractions and countup (if the order is short-cut) are carried out until this order of the multiplier register 209 is at zero. Sensing, shifting, successive accumulations or subtractions and countdown or countup are carried out for each of the remaining lower orders of the multiplier register, at the end of which time, the pin carriage 205 and single tooth gear 346 are in a "home" position lined up with the lowest order value in the multiplier register 209. Still under control of the program unit 229, the product developed in the accumulator register 207 is cleared out of the accumulator register and printed in red on the tape 328 followed by the symbol T.

Subtotal = key

The subtotal = key 114 (ST=) is provided to actuate the program unit 229 to initiate subtotal = multiplication operation which is similar to the total = multiplication initiated with the total = key 112. At the end of a subtotal = multiplication, the product developed in the accumulator register 207 is subtotalled, instead of totaled, out of the register 207 and printed in red on the tape 328 followed by the symbol S. The product, during subtotaling, is not cleared out of the accumulator register 207 and is available for further accumulations or transfer as a multiplier to the multiplier and counter registers 209 and 211 in the manner discussed. The ST= key 114 is latched down whenever depressed and is released upon depression of any control key 201 or 203 of the machine or any value key 101.

Negative = key

The negative = key 116 (N=) is provided to actuate the program unit 229 to initiate a negative total = multiplication operation during which a multiplicand value is printed in black on the tape 328 followed by the symbol == and then successively entered into the accumulator register 207 negatively to form a product which is printed on the tape 328 in red followed by the symbol T-. In all other respects, the multiplication operation initiated by the N= key 116 is identical to that initiated by the T= key 112.

The negative = key 116 may also be used to initiate a negative subtotal = operation when the ST= key 114 is depressed simultaneously therewith. Such an operation is the same as a negative total = operation except that the symbol S- is printed in red following the product

and the product is not cleared from the accumulator register.

SPECIFIC DESCRIPTION

ADDING MACHINE KEYS AND MECHANISM

Specific structure including value keys 101 (FIG. 2), the pin carriage 205, the accumulator register 207, accumulator register controls 227 and rack assemblies 300 (FIG. 3) are used for carrying out adding machine functions and can be related to individual adding machine control keys 201 (FIGS. 2, 6, and 7). The description of the specific structure is therefore associated by sub-headings as much as possible, in the following specific discussion, with the individual keys. Before proceeding with the specific description, however, a general description of the adding machine structure, substantially in the order presented in the specific description, is appropriate. Briefly, depression of any of the adding machine control keys 201 (FIGS. 2, 6, and 7) actuates mechanism which starts a motor (not shown) and engages a main clutch 801 (FIG. 8) thereby connecting a motor shaft 802 with the main operating shaft 330 (FIG. 3) for a cycle of operation. Near the end of the cycle, the actuated mechanism is restored to the normal position. In addition, accumulator register controls 227 (FIG. 2) including main control slides 901 (FIG. 9) are actuated by depression of a control key 201, the slides 901 being driven leftward to be stopped in a particular position which corresponds to the actuated key 201. The position in which the control slides 901 are stopped is further controlled, after depression of a control key 201, by mechanism responsive to whether or not a valve is in the pin carriage 205, for the purposes mentioned previously in the General Description, and by mechanism responsive to the debit or credit condition of the accumulator register 207. The position in which the main control slides 901 are stopped is therefore under control of the keys 201, the pin carriage 205 and the accumulator register 207. After such positioning, other mechanism of the accumulator and register controls 227, which is responsive to the position of the main control slides 901, drives the accumulator register 207 into and out of engagement with the rack assemblies 300 at the proper times and for the necessary periods to carry out the operation called for by a depressed key 201. The slides 901 also trigger mechanism for controlling the printing mechanism 214 to print symbols corresponding to the depressed key.

Add-total key, add function

Specifically, depression of the add-total key 103 (FIG. 1) with a value in the pin carriage 205 starts the motor and engages the main clutch 801 (FIG. 8) initiating an add cycle during which the value in the pin carriage 205 is printed and entered into the accumulator register 207.

Motor starting and main clutch engagement.—Depression of the add total key 103 (FIGS. 6 and 7) lower a depending keystem 601, forcing a stud 603 extending from the keystem downward into engagement with the right end of an add-total trip slide 605. A slot 607 formed in the trip slide is forced thereby out of engagement with ear 608 for movement forward, or leftward in FIG. 7, under the urging of a spring 609. The left end of the trip slide 605 is bent for engagement with a clutch starting bail shaft 701 which is mounted in right and left arms of a clutch starting bail 703 (FIGS. 7 and 10). As the trip slide 605 is moved forward, the shaft 701 and bail 703 are driven CCW about a shaft 705 (FIGS. 7 and 11) by the trip slide. The shaft 701 (FIG. 11) extends leftward through a right arm 1101 of a second clutch starting bail 1103 so that the bail 1103 and the bail 703 are rocked CCW together by the trip slide 605. A left arm 1104 of the bail 1103 is mounted on a frame shaft 1114 and is rocked CCW with the bails 703 and 1103. An ear 1260 that extends from the arm 1104 is rocked thereby against an

interponent 1201 (FIG. 12). The interponent 1201 is also mounted on the shaft 1114 and is rocked by the arm 1104 CCW out of engagement with an ear 1244 of a front starting lever 1203 which is pivoted on another frame shaft. This permits a spring 1205 to rock the lever 1203 CW and carry a front starting link 1206 which is pivoted on the lower end of the lever 1203, leftward. During such leftward movement, a slot 1208 in the right end of the link 1206 engages a stud extending from a back starting lever 1210, driving the lever 1210 CW against a spring 1212. Clockwise rocking of the lever 1210 disengages an ear 1214 formed thereon from a shoulder 1256 formed in a back starting link 1216, permitting the link 1216 to move leftward under the urging of a spring 1218. The right edge of a slot 1220 in the right end of the link 1216 engages a stud on a main clutch latch 1222, driving the latch CW against a spring 1124. A shoulder 1226 which is formed in the latch 1222 (FIGS. 8 and 12) is disengaged thereby from a stud 803 on a main clutch dog 805. This permits a spring 807 to rock the dog CW about a frame shaft to a position in which a roller 809 is against a main clutch cam 811, which cam is keyed to the main operating shaft 330. Clockwise rocking of the main clutch dog 805 also drives a motor switch holding link 813, which link is engaged with the stud 803, leftward. A motor switch lever 815 is mounted on a frame shaft 816 and is pivoted at 818 to the right end of the link 813. The lever 815 is rocked CW by the link 813 against a spring 817. This moves the lever 815 from beneath an ear 819 on a cover interlock lever 820, which lever is also mounted on the shaft 816, permitting the lever to rock CW under gravitational force. An actuating pin 822 which is in engagement with the ear 819 is permitted thereby to be driven downward by an upper leaf spring 824 of a motor starting switch 826. A pair of switch contacts 828 close thereby and start the motor (not shown). If the machine cover is removed from the machine 100, a cover stud 830 is released by means not shown to rise to a position in engagement with the right end of the cover interlock lever 820, thereby preventing the contacts 828 from closing and the motor from starting even though the motor switch lever 815 is rocked CW.

With the machine covers in place, however, the contacts 828 close when the lever 815 is rocked CW, starting the motor. The motor shaft 802 drives a main clutch gear 832 through pinions 833 and 835. The gear 832 is freely mounted on the shaft 330 along with a main clutch ratchet 834, which is suitably fastened to the gear 832 for rotation therewith whenever the motor is running. Since the main clutch dog 805 was released CW to engage the cam 811, an ear 836 on a right arm of the dog 805 is out of engagement with the tail of a main clutch pawl 838. The pawl is pivoted at 841 to the main clutch cam 811 and is freed thereby to move into engagement with the main clutch ratchet 834 by means of a spring 840 between the pawl and the cam. When so engaged, the main clutch ratchet 834 drives the main clutch cam 811 and the main shaft 330 CCW to which the cam is keyed. When the pawl is not engaged with the ratchet, the stud 841 is normally engaged with a tail of a cycle completion latch 843 and is disengaged whenever the pawl and ratchet are engaged to drive the cam 811 and shaft 330. Upon disengagement, the latch 843 is rocked CCW by a spring 845 to a position in which a shoulder 847 engages and latches the link 813 in the leftward position, to which position it is driven to start the motor, even though the main clutch dog 805 be restored to the CCW latched position, as discussed hereinafter.

Near the end of the cycle, a restore slide 4922 (FIG. 12) is driven rightward, by means discussed hereinafter. A starting restore link 1230 that is pivoted to the restore slide 4922 at 1252 is driven rightward with the slide against a spring 1232 to a position in which the left edge of a slot 1234 engages a stud 1236 on a starting restore lever 1238, driving the lever 1238 CCW and bringing an

ear 1240 on the left end of the lever into engagement with a tail 1242 on the arm 1104. The bail 1103 is driven CW thereby and restored to the position shown from the CCW actuated position previously discussed. When the arm 1104 is rocked CW, the shaft 701 (FIG. 7) and the clutch starting bail 703 are carried CW therewith. The shaft 701 is driven against the add-total trip slide 605, driving the trip slide rightward to permit the trip slide 605 to spring upward and re-engage the ear 608. The starting interponent 1201 (FIG. 12), however, is held to the right of the ear 1244 on the front starting lever 1203 and remains in that position. Near the end of the rightward stroke of the restore slide 4922, the left edge of a slot 1246 in the starting restore link 1230 engages the stud 1248, driving the front starting lever 1203 CCW to a position which permits a spring 1250 to rock the starting interponent 1201 CW to the position shown in FIG. 12. Also, during the rightward stroke, the stud 1252 engages a shoulder 1254 on the link 1216, driving the link rightward to a position which permits the ear 1214 to rock CCW to the left of the shoulder 1256 to hold the link 1216 in the position shown when the slide 1216 is moved leftward.

As the main clutch cam 811 continues rotating CCW, the main clutch dog 805 is driven CCW, relatching the main clutch latch 1222 (FIGS. 8 and 12) in the position shown. Still further rotation of the main clutch cam 811 brings the tail of the main clutch pawl 838 into engagement with the ear 836, driving the pawl out of engagement with the ratchet 834 and thereby stopping rotation of the main shaft 330. As the main clutch cam 811 rotates to the position shown in FIG. 8, the stud 841 engages an upward extending nose 849 on the cycle completion latch 843, driving the latch 843 CW out of engagement with the motor switch holding link 813. This permits the link 813 to be spring urged rightward by the spring 817. The contacts 828 are opened thereby and the motor is stopped.

Keyboard sensing slide escapement and positioning of accumulation register.—In addition to starting the motor and engaging the main clutch 801, depression of the add-total key 103 releases a keyboard sensing slide 1001 (FIGS. 10, 11 and 13) to condition the control slides 901 (FIG. 9) to be driven to a particular position for control of the accumulator register 207 (FIGS. 2 and 3).

When the clutch starting bail left 1103 (FIG. 11) is rocked CCW by release of the add-total trip slide 605 (FIG. 6), in the manner discussed, the right arm 1101 of the bail 1103 is carried out of engagement with a shoulder 1106 on the keyboard sensing slide 1001 to permit the slide 1001 to be pulled rightward by a spring 1003 FIG. 10. As the keyboard sensing slide 1001 moves rightward, a stud 1005 (FIGS. 10 and 13) which extends from the slide engages the left end of an auxiliary keyboard sensing slide 1007, driving the slide 1007 rightward. A control slide blocking element 1301, having a pin 1303 extending into a slot 1305 in the right end of the auxiliary sensing slide 1007, is driven CW by the slide to a position 1301-A. The control slide blocking element 1301 (FIG. 9) is thereby in a position to block the control slides 901 in an "add" position when the slides are driven leftward during the cycle.

The control slides 901 are driven leftward by a main gear sector 903 which is normally held in the position shown in FIG. 9 and which is driven CW during 0 to 48° of a cycle by a spring 905. The sector 903 is normally held by a cam follower 907 with a roller 909 against a cam 1401 (FIG. 14) which is mounted on the main cam shaft 330. When the cam 1401 rotates to a low portion, follower 907 and gear segment 903 follow the cam until blocked by means presently described. The cam 1401 then restores the sector 903 to the position shown during the period from 230° to 320°.

Such CW rocking of the main gear sector 903 drives a slide gear 911 CCW, which gear in turn drives a main control slide leftward. During an add cycle, a control slide latch 915 is rotated CW by means discussed herein-after to a position 915-A. This leaves the main control slide 913 free to be driven leftward by the spring 905 to a position in which the control slide blocking element 1301, being in the add position 1301-A, engages and blocks an add surface 916 on the main control slide 913, blocking the slide 913 in an add position from further leftward movement. During this period, the slide gear 911 drives a vertical slide 918 to a corresponding add position 918-A. The sector 903 is stopped also in an add position, and consequently, a stud 919, which extends from the sector 903 into engagement with a camming slot formed in the left end of a mode lever 921, drives the lever CCW about a frame shaft. A mode bail 923, having a stud 922 engaged in a slot in the right end of the mode lever 921, is rocked CW to an add mode position 923-A. A hook driver link 925, pivoted to the mode bail 923 at 924, is driven downward with the mode bail to a position in which a hook driver pin 926, extending from the link 925 is carried to an add mode position 926-A. At 145° of the cycle, an add mode follower 928, having a roller 929 in engagement with a cam 1403 (FIG. 14) that is keyed to the main shaft 330, is driven CCW by the cam 1403, forcing a follower nose 930 (FIG. 9) against the hook driver pin 926. The pin 926, as viewed from the top in FIG. 15, extends from the hook driver link 925 into the path of the nose 930 and into engagement with a slot 932 formed in a hook follower 933. As the nose 930 is driven against the pin 926, which is in position 926-A, the pin drives the follower 933 CCW. A stud 935 extends from the hook follower 933 into engagement with a slot in the right end of a hook driver 937 for forcing the driver 937 rightward as the hook follower 933 is rocked CCW. An uphook 939 and a downhook 941 are pivoted on the hook driver 937 at points 942 and 943 respectively and are carried rightward with the driver. A stud 945 extends from the hook driver 937 into blocking engagement with the right ends of an up slide 947 and a down slide 948. A spring 950 is connected between the uphook 939 and the upslide 947, and a second spring 951 is connected between the downhook 941 and the downslide 948. The springs 950 and 951 force the up and down slides rightward against the stud 945. As the hook driver 937 is driven rightward during an add cycle, the up and down slides 947 and 948 are urged rightward through the respective springs 950 and 951. The vertical slide 918 is normally in a "home" position in which it is shown. A front view of various positions of the lower portion of the slide is shown in FIG. 16. In the home position the slide is in the path of ears 953 and 954 formed in the left ends of slides 947 and 948 respectively. It will be remembered, however, that the vertical slide 918 was driven to the add position 918-A when the slide 913 was driven leftward, and therefore, as shown in FIG. 16, a notch 1601 formed in the slide 918 lies opposite the ear 953, permitting the upslide 947 to be carried rightward with the hook driver 937. The ear 954, however, is opposite a solid portion of the vertical slide 918. The downslide 948 is therefore blocked from movement rightward with the hook driver 937. As the upslide 947 is carried rightward through the notch 1601, the left end of the uphook 939 engages a stud 956 on an accumulator plate 957, driving the plate 957 CW, starting at 165°. The accumulator plate 957 is keyed to a connecting shaft 959 which is geared by means not shown to a shaft 1802 (FIG. 18) at a 1 to 1 ratio for CW movement therewith. An accumulator box cam 1800 which is keyed to the shaft 1802 is rocked CW by the uphook 939. The accumulator register supporting shaft 310 (FIGS. 3 and 18) is driven upwards by the box cam 1800, carrying the numeral wheels 306 into engagement with the upper rack teeth 348 (FIG. 3). This action is indicated by the curve on

line 17A (FIG. 17). Engagement of the accumulator register 207 with the racks 303 is completed at 180°, as indicated on line 17A, the racks 303 at this time being fully rightward as indicated on line 5A (FIG. 5) and in value representing position.

As the hook driver 937 (FIG. 9) and downhook 941 are driven rightward, the spring 951 urges the downslide 948 rightward into blocking engagement with the solid portion of the vertical slide 918. However, since the downslide 948 is blocked from further rightward movement, a camming shoulder 961 formed on the downslide 948 lies in the path of a stud 963 on the downhook 941. As the downhook 941 is carried rightward, the stud 963 engages the shoulder 961 and is cammed CCW, rocking the left end of the downhook 941 out of the path of engagement with a lower stud 964 extending from the accumulator plate 957, thereby permitting the plate 957 to rock CW under the influence of the uphook 939 in the manner discussed above. A plate centralizer 966 is spring urged into engagement with a lower surface of the accumulator plate 957 to maintain the plate 957 in whichever position the plate is driven; CW, CCW or centralized.

At the beginning of every cycle, including the beginning of an add cycle discussed above, the accumulator register 207 is centralized, from 20°-35° as indicated on line 17A (FIG. 17). In order to centralize register 207 during this period, a centralizer follower 968 having a roller 969 is driven CCW by a cam 1405 (FIG. 14) at 0° at the beginning of every machine cycle and is spring returned CW at 40°. A stud 971 extending from the lower end of the centralizer follower 968 is engaged in a slot in the right end of a centralizer 972. As the centralizer follower 968 is rocked CCW, the centralizer 972 is driven rightward, bringing camming surfaces 973 and 974 on the left end of the centralizer into engagement with either the stud 956 or the stud 964 extending from the accumulator plate 957, whichever stud is to the left of the centralized position. Such engagement occurs at 20° of a machine cycle as indicated on line 17A (FIG. 17), centralization of the plate 957 and box cam 1800 (FIG. 18) being completed at 35°.

In order to maintain the accumulator register numeral wheels 306 (FIG. 18) aligned in the position to which they are driven by the racks 303 during an add cycle or any other cycle, an accumulator register numeral wheel centralizer 1801 is forced into engagement with all of the wheels 306 whenever the accumulator register 207 is in the centralized position. The centralizer 1801 extends rightward and leftward into slots 1803 in right and left accumulator register slide plated 1805, only the right plate being shown in FIG. 18. A guide roller 1807 is carried on each end of the centralizer 1801 and is forced by springs 1808 into engagement with a camming surface 1809 formed in the machine frame. The accumulator register shaft 310 extends through the accumulator register slide plate 1805 and carries the plate 1805 upward and downward as the accumulator register 207 is carried into and out of engagement with the upper and lower rack teeth 348 and 350 (FIG. 3). As the accumulator slide plate 1805 is moved upward or downward, the centralizer 1801 is carried therewith so that the guide roller 1807 is cammed leftward by the frame surface 1809. The centralizer 1801 is forced leftward with the rollers 1807, out of engagement with the wheels 306 whenever the register 207 is moved from the centralized position into engagement with the racks 303.

Pin carriage escapement.—The pin carriage 205 (FIG. 19) normally is blocked from escapement leftward by engagement of a raised nine pin 304-9 with a nine pin stop 1901. Depression of any value key 101 (FIG. 1) drives the nine pin 304-9 in that order, as well as the pin 304 corresponding to the depressed key 101, downward, lowering the pin 304-9 from engagement with the nine pin stop 1901. Upon release of the value key to a raised position, the pin carriage 205 is released to be spring urged left-

ward one order to a position in which the nine pin 304-9 in the next order to the right is blocked against the nine pin stop 1901.

Specifically, a nine pin 304-9 (FIG. 20) is driven downward whenever a value key 101 is depressed, as for example, the five key 101-5. Depression of the key 101-5 and associated keystem forces an extension 2101 (FIGS. 20 and 21) against a five pin 304-5, detenting the pin downward. Depression of the key 101-5 also drives a shoulder 2103 against an escapement shaft 2105 which is carried in right and left arms 2001 and 2002 of an escapement bail 2003, driving the bail 2203 CW (FIG. 21) against the urging of a spring 2107. The escapement shaft 2105 is driven against a nine pin driver 2109, forcing the driver 2109 CCW about a frame shaft and driving a nose 2111 against the nine pin 304-9, detenting the pin downward out of engagement with the nine pin stop 1901 (FIG. 19). The pin carriage is spring urged leftward bringing the five pin 304-5 in the next order to the right into engagement with the lowered extension 2101 (FIG. 21) and the nine pin 304-9 in the next order to the right into engagement with the lowered nose 2111. Upon release of the value key 101-5, the extension 2101 and the nose 2111 are spring urged out of engagement with the respective pins by a spring 2130, permitting the pin carriage 205 to move leftward to a position in which the raised nine pin 304-9, in the next order to the right, is blocked against the nine pin stop 1901 (FIG. 19).

Nine pin sensing levers.—In order to prevent the rack assemblies 300 (FIG. 3) which are to the left of the highest order digit represented in the pin carriage 205 from being driven rightward during an add cycle, a nine pin sensing lever 2201 (FIG. 22) is provided to block those assemblies at the zero position. A nine pin sensing lever 2201 is associated with the main member 301 of each assembly 300 in each order. Each lever 2201 is loosely mounted on a shaft 2202 and is urged CCW by a spring 2203. The levers 2201, however, are normally held in the CW position shown by a retracting bail 2205, which underlies a leftward extending arm of each lever 2201. The retracting bail 2205 is loosely mounted on the shaft 2202 by means of right and left arms 2207 to which right and left retracting links 2209 are pivoted. As the assemblies 300 and members 301 are driven rightward by the rack drive shaft 408 (FIGS. 4 and 22), the shaft 408 moves rightward out of engagement with right and left retracting levers 2211 which are pivoted to respective links 2209. This permits the springs 2203 to rock the lever 2211 CW and the retracting bail 2205 CCW. In each order of the pin carriage 205 in which a value has been entered, the nine pin 304-9 is depressed to the dotted outline position indicated. The nine pin sensing lever 2201 in each such order is blocked from CCW movement by engagement with the depressed nine pin 304-9. In those orders to the left of the highest order value in the pin carriage 205, the nine pin 304-9 is not depressed and the nine pin sensing lever 2201 is free therefore to rock fully CCW to a position in which a projection 2213 is stopped against a frame down stop 2215. In this CCW position, a nose 2217, which extends from the nine pin sensing lever 2201 and is angled slightly leftward toward the member 301, is in the path of a stud 2219 extending from the member 301. The rack assemblies 300 associated with the left orders are prevented thereby from being driven rightward and entering a value into the accumulator register 207, while the studs 2219, associated with right orders which represent values, freely pass beneath the noses 2217. Upon return of the rack drive shaft 408 leftward to the position shown, all of the elements 2201-2219 are restored to the positions shown.

Zero suppression mechanism.—In order to prevent printing of zeros in orders to the left of the highest order digit, the segments 311 and main members 301 (FIG. 3) in these orders are returned from the zero position in which they are blocked by the nine pin sensing levers 2201

(FIG. 22) to the subzero position in which are shown in FIG. 3. The higher order members 301 are free for such restoration since the locking ears 336 are to the left of the teeth of the toothed racks 337 when the members 301 are blocked in the zero position by the nine pin sensing levers. Each main member 301 is restored to the subzero position by means of an elimination pawl 363. Such a pawl is associated with each print segment 311. The pawls are mounted in right and left side frames 364 (FIG. 3A) on a shaft 365 extending between the frames. The frames are pivoted at 367 on the machine framework. Each elimination pawl 363 is urged CW by a spring 368 connected between the pawl and a blocking arm 369 mounted on the shaft 324. The blocking arm is prevented normally from CCW rotation by a stud 370 extending from the associated segment 311. A second shaft 371 is carried by the frames 364 for blocking a tail which extends from each elimination pawl, thereby maintaining them in the normal position shown in FIG. 3A. A roller 373 extends from each frame 364 into engagement with a camming surface 374 of respective right and left cam plates 375 which are mounted on the shaft 324. The driving means for the cam plate 375 is fully disclosed in the Edwards application mentioned previously in the General Description. Generally, however, the cam plates 375 are rotated CCW at the beginning of each cycle. As the cam plates rotate, the springs 368 urge the rollers 373 against respective cam surfaces 374 to rotate all of the elimination pawls CW about the pivot 367. During the same period, the members 301 are driven rightward to value positions or against nine pin sensing levers 2201; and the printing segments 311 are driven CCW to corresponding positions. At approximately 105° of the cycle (line 5A, FIG. 5), the members 301 to the left of the highest order digit are blocked in zero positions and the other members are driven to value representing positions the highest of which is beyond zero. At this time the elimination pawls 363 which are associated with the orders to the left of the highest digit are free to rotate to a position 363-A (FIG. 3).

As the cam 375 continues to rotate CCW, the rollers 373 engage a slot 377 in the cam, driving the elimination pawls 363 CW against a shoulder 378, which is in the position 378-A on each segment 311 in the zero position. These segments, as well as the main members 301, are driven CW by respective pawls 363 from the zero positions to subzero positions as the pawls continue to rock CW. The segment 311 which represents the highest order digit is rotated CCW by the main member 301 beyond the zero position. With a segment 311 in a position from 1-9, the stud 370 is CCW far enough to permit the blocking arm 369 to rotate to a position 369-A. During such rotation a shoulder 379 on the arm 369 engages the blocking pawl before the pawl can rotate to the position 363-A. This prevents engagement of the pawl with the shoulder 378 and therefore prevents blocking or rotation of the highest order segment by the pawl. The pawls are arranged side by side on the shaft 365 as shown in FIG. 3B, with ears 380 extending leftward over the next higher order pawl. Consequently, when the pawl associated with the highest order digit is held away from the shoulder, all pawls to the right are also held away from respective shoulders through engagement of the ears 380. This permits printing of zeros in lower orders while the higher orders are suppressed.

Pin carriage clearance.—Near the end of an add cycle the pin carriage 205 (FIGS. 3, 23, and 23A) is cleared by driving the carriage rightward (FIG. 23), forcing any pins 304 in the lower detented position 304-A into engagement with a camming surface 2300 on the left end of a clear plate 2301 (FIGS. 23 and 24) and detenting them to the upper detented position. At the same time, the clear plate 2301 is driven leftward to ensure restoration of all of the pins 304 and to eliminate the necessity of a long rightward stroke of the pin carriage 205. Normally, the

rightward motion of the pin carriage 205 is the result of two forces acting on the carriage. First, the pin carriage 205 is positively driven rightward to a position in which a row of pins 304-X engage the surface 2300. Normally, the next two rows of pins 304-Y and 304-Z are carried rightward against the surface 2300 by the momentum of the carriage 205 during a period of deceleration not under the influence of a clearance cam 2605 (FIG. 26), referred to hereinafter. During certain operations, the pin carriage 205 may contain a value in one or all of the orders 204-X-Z and be in a position immediately to the left of the clear plate 2301 so that the cam does not drive the carriage 205 at all. Rather than provide additional space for a longer stroke of the pin carriage 205 and construct a wider overall machine, the clear plate 2301 is driven leftward beneath the rows of pins 304-X-Z to ensure clearance.

The power for driving the pin carriage 205 during clearance is transmitted through a main gear 2501 (FIG. 25) which is keyed to the main shaft 330. The main gear 2501 is driven CCW during the add cycle, driving a ratchet gear 2503 which is loosely mounted on a shaft 2504, CCW through an idler gear 2505. A ratchet 2507 formed on the ratchet gear 2503 normally is engaged with a clutch pawl 2509 which is pivoted on a pawl disc 2511. The pawl is urged into engagement with the ratchet 2507 by a spring 2513 between the pawl 2509 and the pawl disc 2511. Both the pawl disc 2511 and a driving gear 2515 are keyed to the shaft 2504 and are driven CCW as long as the clutch pawl 2509 remains in engagement with the ratchet 2507.

The driving gear 2515 drives a cog gear 2517 through a gear train comprising a large idler gear 2519 and a small gear 2521, the small gear 2521 being pinned to a shaft 2523 to which the cog gear 2517 is also pinned. The cog gear 2517 (FIG. 26) drives a cog plate 2601 which is keyed to a shaft 2603. A pin carriage clearance cam 2605 is also keyed to the shaft 2603 and is driven CW thereby. A pin carriage clearance cam follower normally is maintained in the position shown with a roller 2604 out of engagement with the cam 2605.

Upon entry of a digit into the pin carriage 205, the follower 2606 is moved a corresponding incremental distance towards the cam 2605 by the following means. The cam follower 2606 is mounted on a frame stud 2607 and is connected by a link 2610 to a sweep arm 2608 which is mounted on a frame stud 2609. The sweep arm 2608 and cam follower 2606 are urged CCW by a spring 2612. The forward end of the sweep arm 2608, however, is engaged with a stud 2614 that extends from a tape pull bail 2616 (FIGS. 23 and 26). The bail 2616 has right and left arms which are slidably mounted on a shaft 2618. An arm 2619 extending from the tape pull bail 2616 is engaged with a pair of tape end clamps 2621 which are suitably fastened to a tape 2623. The tape 2623 (FIG. 23) is guided around guide rollers 2303 and suitably fastened to the pin carriage 205.

Values are entered into the pin carriage prior to machine operation by means of value keys 101. Upon depression of a value key 101 and downward detenting of a nine pin 304-9 (FIG. 19) the pin carriage 205 is released by the nine pin stop 1901 in the manner discussed before to escape one order leftward under the urging of the spring 2612 (FIG. 26). Release of the pin carriage 205 permits the spring 2612 to rock the sweep arm 2608 CCW, carrying the pin carriage clearance cam follower 2606 a corresponding incremental distance towards the surface of the pin carriage clearance cam 2605. Escapement of the pin carriage 205 fully leftward to a full tab position brings the roller 2604 into engagement with cam 2605. During an ensuing cycle which calls for pin carriage clearance, such as an add cycle, the cam 2605 is driven a full 360° CW. As the surface of the cam starts to rise at 270°, as indicated on line 17B (FIG. 17), the cam follower 2606 is driven CW from 270° to 330°. The pin carriage 205

(FIG. 23) is driven rapidly rightward during this period, bringing any detented pins 304-A into engagement with the clear plate 2301, driving them upward to clear the pin carriage. The clear plate is driven leftward during this period, by means discussed hereinafter, to ensure clearance in all orders of the pin carriage.

During certain other cycles, however, which are discussed hereinafter, it is necessary to prevent clearance of the pin carriage. Before 245° of a cycle has elapsed, engagement of the pin carriage clearance cam 2605 with the follower 2606 and clearance of the pin carriage may be prevented by permitting a tail 2525 (FIG. 25) of the clear clutch pawl 2509 to engage a dog bail 2527 which is normally in the path of the tail. The tail 2525 engages the dog bail 2527, forcing and holding it out of engagement with the ratchet 2507, thereby suspending clearance of the pin carriage 205.

In order to carry out pin carriage clearance during an add cycle, however, the dog bail 2527 is rocked CCW out of the path of the tail 2525, permitting the cam 2605 to continue rotating in order to drive the pin carriage 205 rightward. At approximately 200° of every machine cycle, therefore, a carrier 2701 (FIG. 27) is driven leftward, in a manner discussed more fully hereinafter in the "Program Unit" Section. A forward camming edge 2702 of the carrier engages a stud 2704 extending from a latching member 2706 which is pivoted on the machine frame. The member 2706 is cammed CW, carrying a forward ear 2707 out of engagement with a nose 2709 of a holding bail 2710. This permits the bail 2710 to be rocked CW by a spring 2712 to a position 2710-A into engagement with upper surfaces of a group of program plates included in the program unit 229. One such program plate for example is a multiplier plate 2714, having a low upper surface 2716, other plates in the group being similar to, and normally in, substantially the same position as the plate 2714. With all of the program plates in normal positions, as during an add cycle, CW rocking of the holding bail 2710 is effective to rock the dog bail 2527 (FIG. 25) CCW, by means presently described, to permit clearance of the pin carriage 205. During other operations, including multi-cyclic division or multiplication operations, however, one of the program plates may be in a position to present a higher surface to the holding bail 2710 and thereby prevent it from rocking fully CW. In this case, the dog bail 2527 remains in the position shown in FIG. 25, rocking the clear clutch pawl 2509 out of engagement with the ratchet 2507 and suspending clearance of the pin carriage.

When the holding bail 2710 is rocked fully CW against a low plate surface, a wire link 2718 connected thereto is carried leftward. The right end of the wire link is connected to a bell crank 2720 which is rocked CCW thereby about a frame shaft, driving a second wire link 2722, connected to a right arm of the bell crank 2722, upwards. The lower end of the second wire link 2722 (FIG. 25A) is connected to a driving bail 2529 (FIGS. 25 and 25A), rocking the driving bail CCW as the link 2722 is driven upwards. An arm 2530 extends from the bail into engagement with a projection 2532 extending from a live tip 2534. The live tip 2534 is pivoted on a clear link 2536 at point 2538 and is spring urged CCW by a spring 2540, which normally forces an ear 2542 of the live tip 2534 into engagement with the clear link 2536. The right end of the clear link 2536 is connected to the dog bail 2527, enabling the spring 2540 normally to hold the link 2536 rightward and the bail 2527 in the CW position with the projection 2532 against the arm 2530. Clockwise rocking of the holding bail 2710 (FIG. 27) forces the driving bail 2529 CCW (FIG. 25A), driving the arm 2530 against the projection 2532 to carry the clear link 2536 leftward and the dog bail 2527 CCW out of the path of engagement of the tail 2525 extending from the clear clutch pawl 2509. The pin carriage clearance cam 2605 (FIG. 26) is driven thereby a complete 360° during an add cycle,

driving the pin carriage 205 rightward to carry out clearance.

Leftward driving of the clear plate 2301 (FIG. 23) is carried out in response to CCW rocking of a clear cam follower 2544 (FIG. 25). The clear cam follower 2544 has a roller 2545 mounted thereon and is rocked CCW whenever a clear cam 2546 which is keyed to the shaft 2504, is driven along with the pawl disk 2511, a full 360°. During such a cycle, the cam 2546 drives the clear cam follower 2544 CCW at 245°, as indicated on line 17B (FIG. 17), driving a shiftable clear plate drive link 2548, which is pivoted at 2562 to the follower 2544, rightward. A restore bail 2550 is pivoted to the left end of the link 2548 at 2549 and is driven CCW when the link 2548 is driven rightward. A link 2552 (FIGS. 24 and 25) is connected between an upper arm extending from the bail 2550 and an arm of a bell crank 2401 (FIG. 24). The bell crank 2401 is rocked CW and the bail 2550 CCW by rightward movement of the link 2548. A stud 2403 extends from another arm of the bell crank 2401 into engagement with a slot formed in the right end of the clear plate 2301 (FIGS. 23 and 24), driving the plate 2301 leftward to the position 2301-A during every pin carriage clearance.

Repeat add key

Depression of the repeat add key 104 (FIGS. 1 and 6) with a value in the pin carriage 205 initiates an add cycle during which the pin carriage 205 is not cleared. The operation in other respects is identical to the add cycle discussed previously.

Depression of the repeat add key 104 (FIGS. 6 and 7) forces a stud 616 extending from a depending keystem against a repeat add trip slide 612, releasing the slide 612 from a frame bracket ear 618 to permit a spring 620 to drive the slide 612 forward against the clutch starting bail shaft 701 (FIG. 7). At the same time, the end of the trip slide 612 (FIG. 10) is positioned in the path of the keyboard sensing slide 1001. Counterclockwise driving of the shaft 701 by the trip slide 612 carries the bail 703 (FIG. 7), CCW starting the motor, engaging the clutch 801 (FIG. 8) with the main shaft 330, and releasing the sensing slide 1001 for movement rightward in the manner discussed hereinbefore. The keyboard sensing slide 1001 is blocked by the trip slide 612 in a position which maintains the control slide blocking element 1301 (FIG. 13) in a repeat add position 1301-B (FIG. 9). Since a repeat surface 976 on the left edge of the main control slide 913 is in the same, horizontal position as the add surface 916, the main control slide 913 is blocked in the add position. The vertical slide 918 also is blocked in the add position 918-A. All the add functions are carried out as during an add cycle in the manner discussed hereinbefore.

As the repeat add trip slide 612 moves forward, after depression of the repeat add key 104 (FIGS. 6 and 7), a rear rightward extending arm 614 drives a pin carriage disabling lever 707 (FIGS. 7 and 25) CCW through a connecting link 709. A pin 2554 extends from the lower end of the disabling lever 707 into engagement with a slot in the live tip 2534, driving the live tip and projection 2532 CW out of engaging relationship with the driving bail 2529. The driving bail 2529, when driven CCW (FIG. 25A) in the manner discussed in the "Pin Carriage Clearance" Section, is idly rocked CCW, leaving the dog bail 2527 in a position to engage the tail 2525 and thereby disengage the pawl 2509 from the ratchet 2507 prior to 245° of rotation of the shaft 2504, i.e. prior to the rise of the clear cam 2546 (FIG. 25) and therefore the pin carriage clearance cam 2605 (FIG. 26) as indicated on line 17B (FIG. 17). At the point of engagement of the tail 2525 with the bail 2527, a detent 2556 in the disk 2511 is opposite a centralizer 2558 which is spring urged at all times against the disk 2511. The roller 2558 propels the disk CCW when moving into engagement with the notch 75 2556, thereby assisting in the disengagement of the clutch.

The roller then holds the disk 2511 and the shaft 2504 in the angular position reached when the pawl 2509 and the ratchet 2507 are disengaged. With the shaft 2504 stopped from further rotation, the clear cam 2546 and the pin carriage clearance cam 2605 (FIG. 26) are prevented from rotating further, thereby suspending rightward driving of the pin carriage 205 (FIG. 23) and leftward driving of the clear plate 2301.

At the end of a repeat add cycle, the repeat add trip slide 612 is relatched with the ear 618 in the manner discussed before under "Motor Starting and Main Clutch Engagement." As the repeat add trip slide 612 is driven rearward for relatching, the live tip 2534 is rocked CCW to the position shown with the projection 2532 in the path of the arm 2530.

Subsequent depression of the repeat add key 104 initiates similar repeat add cycles. Normally after the last repeat-add cycle, the subtotal-correction key 105 (FIG. 1) is depressed, initiating a correction cycle during which the pin carriage 205 is clear in the normal manner. Alternatively, the add-total key 103 may be depressed to initiate an additional normal add cycle during which the pin carriage is cleared.

Repeat subtraction.—Depression of the repeat add key 104 (FIGS. 6 and 7) simultaneously with the minus key 107 initiates a repeat subtraction cycle during which the pin carriage 205 is not cleared. Depression of the minus key 107 forces a stud 622 extending from a depending keystem against a minus trip slide 624, releasing the slide 624 from engagement with a frame bracket 625 for movement forward to initiate a minus cycle. Since the minus trip slide 624 (FIG. 10) lies to the left of the repeat add trip slide 612, the keyboard sensing slide 1001 engages the minus trip slide 624 and not the repeat add trip slide 612. The control slide blocking element 1301 (FIG. 13) is positioned thereby in a minus position 1301-C (FIG. 9) to carry out a minus cycle more fully discussed hereinafter. Since the repeat add trip slide 612 was also released to move forward, the live tip 2534 (FIG. 25) is rocked CW, out of engagement with the driving bail 2529 thereby preventing rotation of the cams 2546 and 2605 (FIG. 26) and clearance of the pin carriage 205 during a minus cycle of a repeat subtraction.

Add-total key, total debit function

A total debit operation is initiated when the add-total key 103 (FIGS. 1 and 6) is depressed if there is no value in the pin carriage 205 (FIG. 3) and if there is a positive or debit value in the accumulator register 207. This operation is distinguished from an add operation which is initiated by depression of the add-total key 103 after a value is entered into the pin carriage 205. Depression of the add-total key 103 (FIG. 6) releases the add total trip slide 605 to move forward, in the manner discussed before under "Add-Total Key, Add Function." This starts the motor and positions the control slide blocking element 1301 (FIG. 13) in the position 1301-A (FIG. 9). With no value in the pin carriage 205 the control slide latch 915 is maintained, by means discussed hereinafter, in the CCW position in which it is shown. Consequently, as the main control slide 913 is driven leftward in the manner discussed before, the control slide latch 915, which is pivoted on a total slide 977, is engaged by a shoulder 978 on the main control slide 913. The total slide 977 is therefore driven leftward with the main control slide 913. The slides 913 and 977 are blocked from further leftward movement when a total debit surface 979, along the left edge of the total slide 977, engages the control slide blocking element 1301 which is in the position 1301-A. With the slides 913 and 977 blocked in this position, the vertical slide 918 is in a total position 918-B. The mode bail 923 is not driven and remains in a total mode position, i.e. the position shown in FIG. 9. The hook driver link 925 and the hook driver pin 926 are therefore not moved and remain in the positions shown.

During the first 40° of the total cycle, as indicated on line 17C (FIG. 17), the accumulator register 207 is centralized, as during an add cycle, discussed hereinbefore. At 40° of the cycle, a total and sub-total follower 1501 (FIG. 15) is driven CCW (FIG. 9) by a cam 1407 (FIG. 14) in engagement with a roller 1408 extending from the follower 1501. The cam 1501 is driven CCW thereby against the pin 926. Since pin 926 extends through the slot 932 in the hook follower 933, the follower 933 is driven CCW, forcing the hook driver 937, the up and downhooks 939 and 941, and the up and downslides 947 and 948 rightward, in the manner discussed hereinbefore. Since the vertical slide 918 is stopped in the total position 918-B (FIGS. 9 and 16), the ear 953 on the upslide 947 is free to move rightward through an upper notch 1603 in the vertical slide 918. The downslide 948, however, is blocked from rightward movement by engagement of the ear 954 with a solid portion of the slide 918. The uphook 939, therefore, engages the stud 956 rocking the accumulator plate 957 CW, driving the accumulator register 207 (FIGS. 3 and 18) upward into engagement with the upper teeth 348 during the period from 50° to 70° of the cycle as indicated on line 17C (FIG. 17).

As the rack assemblies 300 (FIG. 3) are driven rightward by the shaft 408 (FIG. 3), during the period indicated on line 5A (FIG. 5) and in the manner discussed hereinbefore, the value in the accumulator register 207 is transferred to the racks 303, zeroizing the register 207. In order to carry out such transfer and zeroizing, a carry-blocking element 1811 (FIG. 18) is associated with each numeral wheel 306. The elements 1811 are maintained in the same relative horizontal position with the accumulator register shaft 310 and numeral wheels 306 whenever the register is raised or lowered. At times, the element 1811 is shifted leftward to a position in which radial surfaces 1811-A and 1811-B block a tens carry tooth 1821 extending from the numeral wheel 306. This prevents the wheels 306 from being rotated beyond zero positions.

To maintain the same relative horizontal positions, the carry blocking elements 1811 are mounted on a shaft 1813 which is carried in slots in right and left accumulator slide plates 1805, only the right plate being shown. The accumulator register shaft 310 is also mounted in the plates 1805. In order to shift the carry-blocking element from the position shown, leftward to a position to block the tooth 1821, the shaft 1813, which is carried in a vertical slot 1817 in right and left total block slides 1819 (only the right slide being shown), is driven leftward during a total cycle by a cam 1410 (FIG. 14). As the cam 1410 is rotated CCW a roller 1412 (FIGS. 14 and 28) which is pivoted on a lever 2801 is rocked CW about a frame shaft 2803, driving a total power link 2805, which is pivoted to the lever 2801, rightward. During a total or subtotal cycle, the total power line 2805 is maintained as shown by means discussed hereinafter, with a shoulder 2807 positioned to engage a total control stud 2809. During digitation cycles, as more fully discussed hereinafter, the total power link 2805 is lowered so as not to engage the stud 2809 when driven rightward. During a total cycle, however, the shoulder 2807 engages the stud 2809 (FIGS. 28 and 29), which extends from an upper arm 2901 and is pinned to a shaft 2903, rocking the shaft 2903 and a lower arm 2905, also pinned to the shaft 2903, CW. A lower total power link 2907 is connected between the arm 2905 and a total box cam 1823 (FIG. 18). As the total power link 2907 is driven leftward the total box cam 1823 is rocked CW against the urging of a spring 1825. The cam 1823 is keyed to a shaft 1824 to which a left total box cam (not shown) is also keyed. The box cam 1823 is engaged with a shaft 1827 which extends from the total block slide 1819 and thereby drives the slide 1819 leftward as the cam 1823 is rocked CW. Since the shaft 1813 is engaged with the vertical slot

1817 in the total slide 1819, the carry-blocking elements 1811 are moved leftward to a position in which the upper radial surface 1811-A of each element 1811 is in a position to block the associated tens carry tooth 1821 extending from each numeral wheel 206 without rocking the carry-blocking elements 1811 about the shaft 1813. Such blocking stops the wheels 306 in the zero position and the racks 303 (FIG. 3) in a position representing the value in the wheels 306 before being driven to zero.

With the racks 303 stopped in value positions, the printing segments 311 are driven to corresponding value positions in the manner discussed and printing carried out as fully discussed later.

During such printing, a "T" is printed in red to the right of the total value. A symbol printing segment 311 (FIG. 2) bears the symbols S, T, Q, =, +, RM and X instead of numerals and is driven to selective symbol positions by the shaft 408 (FIG. 3), an associated symbol rack 3001 (FIGS. 30 and 30A), and a releasable connection in the same manner as the other segments discussed hereinbefore. In order to stop the symbol rack 3001 in a position to print a "T" during a total cycle, a symbol step plate 3003 is positioned with a total step 3005 opposite a projection 3007 which extends down from the left end of the rack 3001. During the rightward stroke of the rack 3001, the projection 3007 is blocked by the step 3005. This blocks the rack 3001 and the symbol segment in the total position with the symbol "T" on the symbol segment in the printing position. The rack 3001 is restored with the racks 303 in the manner discussed.

To position the symbol step plate 3003 with the step 3005 opposite the projection 3007, the keyboard sensing slide 1001 (FIG. 13) is released to move rightward to the position in which it is blocked by the add-total trip slide 605 (FIG. 10) in the manner discussed. During such movement, an ear 1307 (FIG. 13) on the slide 1001 permits a restore lever 1309, normally held CCW by the ear 1307, to be rocked CW by a stud extending from a symbol slide 1311 (FIGS. 13 and 13A), which slide is spring urged leftward by a spring 1313. The symbol slide 1311 is moved leftward thereby to a position in which it is blocked by a symbol latch 1315. The symbol latch 1315 (FIG. 13A) is driven rightward during a total cycle to release the symbol slide 1311 for further movement leftward. The latch 1315 is driven rightward by means of a total stud 1317 (FIGS. 9 and 13A) which extends from the main slide 913. As the main slide 913 is driven leftward during the total cycle in the manner discussed before, the total stud 1317 is driven against a right arm 1319 which is keyed to a shaft 1321. The shaft 1321 is rocked CCW thereby. A segment 1323 which is also keyed to the shaft 1321 is rocked CCW therewith. A stud 1325 extends from the segment 1323 into engagement with the right end of the symbol latch 1315, driving the latch out of engagement with the symbol slide 1311 as the main slide 913 is driven leftward. With the symbol latch 1315 rightward, the symbol slide 1311 is free to move leftward (FIG. 13) under the urging of the spring 1313 to a position in which an ear 1327 is blocked against a total surface 1329 on a symbol plate 1331. The symbol plate is driven to a position which brings the total surface 1329 opposite the ear 1327 when the sensing slide 1001 is released for movement rightward to initiate the total cycle. The symbol plate 1331 is driven upward by a stud 1350 which extends from the control slide blocking element 1301 into engagement with a slot in the symbol plate 1331. As the element 1301 is driven CW by the slide 1001, a fork 1333 extends from the symbol slide 1311 into engagement with a stud 1335 on a lever 1337 (FIGS. 13, 13A and 30). Upon leftward movement of the symbol slide 1311, as discussed above, the lever 1337 (FIG. 30) is driven CW against a stud 3009 which extends upward from the symbol step plate 3003, driving the step plate 3003 to the position in which the total step 3005 is opposite the projection 3007. In this position, the step 3005

blocks the symbol rack 3001 and symbol segment in a position which permits the symbol "T" on the segment to be printed on the tape 328 in a manner more fully discussed hereinafter.

During a total cycle, it is necessary that all of the rack assemblies 300 (FIG. 3) be driven rightward to a position in which they are blocked by the accumulator register 207 when the register is zeroed. In order to prevent the nine pin sensing levers 2201 (FIG. 22), in all orders, from rocking CCW to the position in which each nose 2217 engages respective studs 2219 and blocks rightward driving of the associated rack assembly 300, the retracting bail 2205 (FIGS. 22 and 29) is blocked from rocking CCW when the rack drive shaft 408 is driven rightward in the manner discussed hereinbefore in the "Nine Pin Sensing Lever" Section.

As discussed earlier in this section, the total control stud 2809 (FIGS. 28 and 29) is driven rightward, rocking the arm 2905 to a position 2905-A. With the arm 2905 in the position 2905-A, a stud 2909 extending from a right arm 2911 (not shown in FIG. 22) of the bail 2205 is driven against the arm 2905 by the springs 2203, blocking the bail 2205 from further CCW rotation. The retracting bail 2205 therefore maintains all of the nine pin sensing levers 2201 in a CW position during a total cycle, permitting the rack assemblies 300 to be driven rightward to value positions, clear of the nose 2217.

Prior to the leftward stroke of the rack assemblies 300 (FIG. 3) during a total debit cycle, the accumulator register 207 is disengaged from the upper rack teeth 348 and centralized. At approximately 145° of the machine cycle, the cam 1403 (FIG. 14) drives the roller 929 CCW, driving the add mode follower 928 (FIG. 9) CCW. The roller 929 is mounted on a stud 1503 which is fastened to the follower 928 but extends laterally into engagement with a slot 1505 formed in a total mode centralizer 1507. The centralizer 1507 is driven CCW whenever the roller 929 is driven. The mode bail 923 is in the total mode position during a total cycle, i.e. the position shown. A centralizer link 1509 (FIG. 15) is pivoted to a left arm of the mode bail 923. A centralizer pin 1511 extends from the centralizer link 1509 laterally in two directions. The right end of the pin 1511 extends into the path of a nose 975 formed in the total mode centralizer 1507. The left end of the pin 1511 extends into a slot 994 formed in the centralizer follower 968. As the roller 929 is driven CCW, the pin 1503 drives the total mode centralizer 1507 CCW, forcing the nose 975 against the pin 1511, driving the pin CCW. As the pin 1511 is driven CCW, the centralizer follower 968 is driven CCW therewith, forcing the centralizer 972, which is engaged with a pin 971 extending from the centralizer follower 968, rightward. As the centralizer 972 is driven rightward, the surface 974 engages the pin 964, extending from the accumulator plate 957, driving the plate CCW to the centralized position shown in FIG. 9. The box cam 1800 (FIG. 18) is rocked CCW thereby to the position shown in FIG. 18, carrying the shaft 310 to the centralized position to lower the accumulator register 207 out of engagement with the upper rack teeth 348 (FIG. 3). Centralization of the register 207 occurs from approximately 160° to 190° of the machine cycle as indicated on line 17C (FIG. 17), such disengagement being prior to the leftward stroke of the rack assemblies 300 indicated on line 5A (FIG. 5). Disengagement of the register 207 with the racks 303 at this time in the cycle leaves the register 207 zeroed, while the value transferred from the register to the racks 303 and the printing segments 311 is printed on the tape 328 followed by a total symbol T.

70 Subtotal-correction key, subtotal function

A subtotal debit cycle is initiated by depression of the subtotal-correction key 105 (FIG. 1) with no value in the keyboard. During a subtotal cycle, the accumulator register 207 (FIG. 3) is maintained in engagement with

the rack teeth 348 during both the rightward and leftward strokes, transferring the value in the accumulator register 207 to the racks 303 and segments 311 for printing during the rightward stroke and re-entering the value into the accumulator register 207 from the racks 303 during the leftward stroke. Depression of the subtotal-correction key 105 (FIG. 6) rocks a subtotal-correction bail 627 which depends therefrom, downward about a shaft 629. A stud 631 which extends from a left arm of the bail 627 is forced against the rear end of a subtotal-correction trip slide 633. This action releases the trip slide 633 from engagement with an ear 634 extending from a frame bracket, permitting the slide 633 to move forward under the urging of a spring 636. The forward end of the trip slide is driven against the shaft 701, rocking the clutch starting bail 703 (FIG. 7) CCW in the manner discussed hereinbefore. The motor is started and the main clutch 801 (FIG. 8) engaged in the manner discussed. Rocking of the bail 703 also releases the keyboard sensing slide 1001 (FIG. 10) for movement rightward under the urging of the spring 1003, in the manner discussed hereinbefore, to a position in which a subtotal-correction shoulder 638 is blocked by the forward end of the subtotal-correction trip slide 633, preventing the slide 1001 from further movement rightward. With the keyboard sensing slide 1001 (FIG. 13) blocked in this position, the control slide blocking element 1301 is in a subtotal-correction position 1301-D (FIGS. 9 and 13). Since there is no value in the pin carriage 205, the latch 915 is maintained by means discussed hereinafter in the normal CCW position. Consequently, as the main control slide 913 is driven leftward in the manner discussed hereinbefore, the shoulder 978 engages the latch 915, driving the latch 915 and the total slide 977 to which it is pivoted, leftward to a position in which a subtotal debit surface 981 is stopped against the control slide blocking element 1301. With the control slides 901 blocked in this position, the vertical slide 918 is blocked in the subtotal debit position 918-C (FIGS. 9 and 16), the mode bail 923 is in the subtotal position 923-B and the pin 926 is in the position 926-B.

As indicated on line 17D (FIG. 17), the accumulator register 207 (FIG. 3) is centralized at the beginning of a subtotal cycle from zero to 40° in the manner discussed hereinbefore. At 35° of a subtotal cycle, the total and subtotal follower 1501 (FIGS. 9 and 15) is driven CCW by the cam 1407 (FIG. 14) into engagement with the hook driver pin 926, pin 926 being in the position 926-B. The pin 926 drives the hook follower 933 CCW, forcing the hook driver 937 rightward, carrying the uphook 939, the downhook 941, the upslide 947 and the downslide 948 rightward in the manner discussed in the "Add-Total Key, Add Function" Section. Referring to FIG. 16, with the slide 918 in the position 918-C, the ear 953 on the upslide 947 is driven rightward through a middle notch 1605 in the slide 918, the downslide ear 954 being blocked against a solid portion of the slide. The accumulator plate 957 is driven CW, thereby raising the accumulator register 207 (FIG. 18) into engagement with the upper teeth 348 (FIG. 3) of the racks 303 in the manner discussed hereinbefore. During a subtotal cycle, the total control stud 2809 (FIG. 28) is driven rightward, as during a total cycle, driving the carry blocking elements 1811 (FIG. 18) leftward to block the tens carry teeth 1821 when the numeral wheels 306 are zeroized.

Since the total control stud 2809 is driven rightward during a subtotal cycle, the arm 2905 (FIG. 29) is rocked to the dotted outline position 2905-A to block the stud 2909 on the retracting bail 2205 (FIGS. 22 and 29) to prevent the bail from rocking CCW. The nine pin sensing levers 2201 are maintained thereby in the CW position, permitting the main members 301 and the rack assemblies to be driven rightward and zeroized under control of the accumulator register 207.

With the register 207 zeroized, the racks 303 and segments 311 are in a position representing the value which

was in the accumulator register 207. Printing of the value is carried out during the periods indicated on line 5C (FIG. 5) in a manner more fully discussed hereinafter.

During the period that the racks 303 and segments 311 are driven rightward by the shaft 408, the symbol rack 3001 (FIGS. 30 and 30A) and symbol segments 311 are driven by the shaft 408 to a subtotal position. This places the symbol "S" on the symbol segment opposite the tape 328 for printing to the right of the subtotal value. Blocking of the symbol rack 3001 in the subtotal position is similar to blocking of the rack 3001 in the total position discussed hereinbefore. During a subtotal cycle, the blocking element 1301 (FIG. 13) is driven to the position 1301-D, thereby raising the symbol plate 1331 to a position in which a subtotal surface 1339 is opposite the ear 1327. After the total stud 1317 (FIG. 13A) is carried leftward by the main control slide 913, driving the symbol latch 1315 rightward out of engagement with the symbol slide 1311, the ear 1327 is driven by the spring 1313 against the surface 1339. The keyboard sensing lever 1337 (FIGS. 13 and 30) is carried CW by the slide 1311, driving the symbol step plate 3003 rightward to a position in which a subtotal step 3011 is opposite the projection 3007. The step 3011 therefore blocks the symbol rack 3001 and the symbol segment in the subtotal position with the symbol "S" opposite the tape 328 (FIG. 3).

Subtotal-correction key, correction function

Whenever it is desired to clear a value entered into the pin carriage 205 without printing the value and without entering the value into a register, a correction cycle is initiated by depression of the subtotal-correction key 105 (FIG. 1). Depression of the subtotal-correction key 105 drives the stud 631 against the subtotal-correction trip slide 633, releasing the slide 633 to drive the clutch starting bail 703 (FIG. 7) CCW, initiating a machine cycle in the manner discussed. As during a subtotal cycle, the subtotal-correction shoulder 638 (FIG. 10) is stopped against the subtotal-correction trip slide 633, positioning the control slide blocking element 1301 (FIG. 13) in the subtotal-correction position 1301-D. Unlike a subtotal cycle, there is a value in the pin carriage 205 (FIG. 2). As a result the control slide latch 915 (FIG. 9) is maintained, by means presently described, in the position 915-A, out of the path of the shoulder 978 on the main slide 913. The main slide 913 is therefore driven leftward to a correction position in which a correction surface 982 engages the control slide blocking element 1301, blocking the main slide 913 from further leftward movement. When the main slide 913 is driven to the correction position, the vertical slide 918 is driven to a correction position 918-D. In moving to the position 918-D, the vertical slide 918 engages a stud 983 on a correction nonprint lever 984, driving the lever CW about a frame shaft. The left end of a link 985 is pivoted to the upper end of the correction lever 984. The right end is pivoted to the upper end of a right arm 3101 (FIG. 31) of a correction nonprint bail 3103 at a point 3105. When the lever 984 is driven CW, the bail 3103 is rocked CW about a shaft 3107 on which it is freely mounted. As the bail 3103 is rocked CW, an ear 3109, which extends from a left arm of the bail 3103, is brought against an enabling lever 3111 mounted on the shaft 3107, maintaining the lever 3111 in the CW position shown.

Normally, during the machine cycle, the enabling lever 3111, is rocked CCW, by mechanism discussed hereinafter, carrying a stud 3113, on an enabling latch 3115, downward into engagement with a notch 3117 in a print cam follower 3119. The enabling latch 3115 is pivoted at 3121 on a print lever 3123 freely mounted on a shaft 3125. The follower 3119 is driven first CCW and then CW about the shaft 3125 every cycle by a pair of complementary cams 3127 and 3129. With the stud 3113 in the notch 3117, as is normally the case, the stud 3113 is

driven against the print lever 3123, forcing the platen 327, in a manner fully discussed hereinafter, against the printing segments 311 to carry out the printing. During a correction cycle, however, the stud 3113 on the enabling latch 3115 is maintained in the position shown, out of the notch 3117, and printing, therefore, is not carried out.

At the beginning of a correction cycle, the register 207 is driven to the centralized position in the manner discussed hereinbefore. With the vertical slide 918 (FIGS. 9 and 16) in the correction position 918-D, the mode bail 923 is in the add mode position 923-A and the pin 926 in the position 926-A in the path of the nose 930. This enables the follower 928 to drive the pin 926 rightward at 160° forcing the hook driver 937 rightward. Referring to FIG. 16, a solid portion of the slide 918 which is in the position 918-D, blocks both the ears 953 and 954 and, therefore, the slides 947 and 948 from movement rightward. Both the hooks 939 and 941 are cammed thereby away from the respective studs 956 and 964 so that the accumulator register 207 is maintained in the centralized position out of engagement with either the upper teeth 348 (FIG. 3) or lower teeth 350 of the racks during a correction cycle.

During a correction cycle the pin carriage is cleared in the manner discussed under "Pin Carriage Clearance."

Minus key

Depression of the minus key 107 (FIG. 1) initiates a minus cycle, during which a value entered into the pin carriage 205 (FIG. 3) is transferred to the racks 303 during the rightward stroke of the racks, in the manner discussed hereinbefore and during the period indicated on line 5A (FIG. 5). During the leftward stroke of the racks 303 the value in the pin carriage is subtracted from the value in the accumulator register 207.

Depression of the minus key 107 (FIG. 6) forces a stud 622 on a depending keystem against a minus trip slide 624, releasing the trip slide 624 from a frame bracket 625 for movement forward to rock the clutch starting bail 703 (FIG. 7). Rocking of the bail 703 causes the motor to start and engagement of the main clutch 801 (FIG. 8) in the manner discussed hereinbefore. The keyboard sensing slide 1001 (FIG. 10) is released to move rightward and is blocked when a minus shoulder 1009 on the slide 1001 engages the minus trip slide 624. The control slide blocking element 1301 (FIGS. 9 and 13) is moved thereby to the minus position 1301-C opposite a minus surface 986 on the main slide 913. Since there is a value in the pin carriage 205, the latch 915 is in the position 915-A. When the main control slide 913 is driven leftward during the cycle, the shoulder 978 misses the ear on the latch 915 and is driven leftward to a minus position in which it is blocked from further movement by engagement of the minus surface 986 with the control slide blocking element 1301. The vertical slide 918 is driven to a minus position 918-E and the mode bail 923 to the add mode position 923-A. The mode bail 923 positions the hook driver pin 926 in the position 926-A in the path of the nose 930 on the add mode follower 928.

At the beginning of a minus cycle, the centralizer 972 (FIG. 9) is driven rightward, centralizing the accumulator register 207 in the manner discussed before. The nose 930, driven by the cam 1403, drives the hook driver pin 926 rightward at 145°. With the vertical slide 918 in the minus position 918-E (FIGS. 9 and 16), the ear 954 on the downslide 948 is driven rightward through the lower notch 1601 in the vertical slide 918, while the ear 953 on upslide 947 is blocked against a solid portion of the vertical slide 918. The down hook 941 engages the lower stud 964 extending from the accumulator plate 957, rocking the plate 957 CCW, forcing the accumulator box cam 1800 (FIG. 18) CCW. The accumulator register 207 is driven downward thereby into engagement with the lower teeth 350 of the racks 303 during the period

indicated on line 17E (FIG. 17). As the racks 303 are driven leftward from the position in which they were stopped by the pins 304, the numeral wheels 306 are rotated CW, subtracting the value represented in the racks 303 from the register 207.

Nonadd key

Depression of a nonadd key 109 (FIG. 1) initiates a nonadd cycle during which an amount entered into the pin carriage 205 (FIG. 3) is printed on the tape 328 followed by a nonadd symbol #, but is not entered into the accumulator register 207, the register 207 being maintained in the centralized position out of engagement with the numeral wheels 306 throughout the cycle. With no value in the pin carriage 205, however, depression of the nonadd key 109 initiates a cycle during which the value in the multiplier register is printed without clearing the register, such a cycle being discussed in another section hereinafter.

Depression of the nonadd key 109 (FIG. 6) rocks a nonadd bail 640, which has a right arm depending from the key, about the shaft 629, forcing a stud 642, which extends from a left arm of the bail, against a nonadd trip slide 644. The slide 644 is disengaged thereby from a frame ear 646 for movement forward under urging of a spring 648. When the slide 648 is moved forward, the clutch starting bail 703 (FIG. 7) is rocked causing the motor to start and engagement of the main clutch 801 (FIG. 8) in the manner discussed hereinbefore. The keyboard sensing slide 1001 (FIG. 10) is released for movement rightward in the manner discussed before, to a position in which a nonadd shoulder 1011 engages the forward end of the nonadd trip slide 644, blocking the slide 1001 in the nonadd position, thereby maintaining the control slide blocking element 1301 (FIG. 13) in the nonadd position shown. Since there is a value in the pin carriage 205, the control slide latch 915 (FIG. 9) is in the position 915-A out of the path of the main control slide 913. The slide 913 is driven therefore leftward to a position in which a nonadd surface 987 engages the control slide blocking element 1301, stopping the slide 913 in a nonadd position. The vertical slide 918 is driven to a nonadd position 918-F (FIGS. 9 and 16) and the mode bail 923 to the add mode position 923-A. With the mode bail 923 in the position 923-A, the pin 926 is in position 926-A so that the hook driver 927 is driven rightward at 145° by the add mode follower 928. Since the vertical slide 918 is in the nonadd position 918-F, both of the ears 953 and 954 of the upslide and downslide 947 and 948 are blocked against a solid part of the slide 918, preventing further movement rightward. The accumulator register 207 (FIG. 18) therefore remains in the centralized position in which it is driven at the beginning of the cycle in the manner discussed hereinbefore.

During a nonadd cycle the value in the pin carriage 205 is transferred only to the racks 303 and segments 311 and printed on the tape 328. Since the element 1301 (FIG. 13) is not moved from the normal position, the ear 1327 is not moved leftward. The lever 1337 therefore does not move and leaves the slide 3003 (FIG. 30) in the position shown with a nonadd surface 3040 opposite the shoulder 3007. The symbol slide 3001 and corresponding segment 311 are blocked thereby in the nonadd position so that the symbol "#" is printed to the right of the nonadd value. The pin carriage is cleared during the cycle in the manner discussed under "Pin Carriage Clearance."

Blank cycle

Depression of either the repeat key 104 (FIGS. 1 and 6) or the minus key 107, with no value in the pin carriage 205 (FIG. 3) initiates a blank cycle during which the accumulator register 207 is maintained in the centralized position throughout the cycle, the rack assemblies 300 are blocked in the zero position, and no printing is carried out. Depression of the key 104 or the key 107 re-

leases either the nonadd trip slide 644 or the minus trip slide 624, initiating a machine cycle in the manner discussed, during which the control slide blocking element 1301 (FIGS. 9 and 13) is positioned in either the repeat or minus positions 1301-B or 1301-C respectively opposite a "blank" surface 988 along the left edge of the total slide 977. Since there is no value in the pin carriage 205, the control slide latch 915 is CCW, in the path of the shoulder 978. As the main control slide 913 is driven leftward during a blank cycle, the shoulder 978 engages the latch 915, driving the total slide 977 against the control slide blocking element 1301, blocking the slides 913 and 977 from further movement. The vertical slide 918 (FIGS. 9 and 16) is driven to a position 918-G in which a solid portion of the slide 918 is opposite the ears 953 and 954, preventing the slides 947 and 948 from being driven rightward and preventing the register 207 from being driven into engagement with the racks 303, in the manner discussed before. The accumulator register 207 is centralized therefore at the beginning of a blank cycle, 20 in the manner discussed hereinbefore, and maintained in this centralized position throughout the cycle.

In order to prevent the printing segments 311 from rotating to the nine position and prevent nines from being printed in all orders during a blank cycle, it is necessary that the nine pin sensing levers 2201 (FIG. 22) be released to the CCW position in which the noses 2217 engage the studs 2219, blocking the rack assemblies 300 and segments 311 in zero positions. Normally, with no value in the pin carriage 205, as during a total or subtotal cycle discussed hereinbefore, the nine pin sensing levers 2201 are maintained in the CW position with the noses 2217 out of the path of the studs 2219, permitting the assemblies 300 to be driven rightward. During a total or subtotal cycle, the stud 2809 (FIGS. 28 and 29) is driven rightward by the total power link 2805, forcing the arm 2905 to the position 2905-A, blocking the stud 2909 and the bail 2205 from CCW rotation. The retracting bail 2205, during a total or subtotal cycle, maintains all of the nine pin sensing levers 2201 in the CW position to permit the studs 2219 and rack assemblies 300 to be driven rightward.

In order to block the rack assemblies 300 in the zero position during a blank cycle, however, the total control stud 2809 is not driven rightward and the arm 2905 is maintained in the CCW position out of the path of the stud 2909. The total power link 2805 is lowered away from the total control stud 2809 by CCW rocking of a total control lever 2811 which has a stud 2813 extending therefrom into engagement with a slot 2815 in the left end of the link 2805. A stud 2817 on the main control slide 913 is normally engaged with a tail 2819 extending from the lever 2811 and holds the lever 2811 in the position shown. When the main control slide 913 is driven to the blank position, the stud 2817 moves to a position 2817-A directly beneath the tail 2819, camming and holding the lever 2811 in a CCW position. The shoulder 2807 is rocked thereby to the position 2807-A, out of engagement with the total control stud 2809. The stud 2809 is not driven by the link 2805 during the cycle so that the arm 2905 (FIG. 29) remains in the position shown when the link 2805 is driven rightward. The retracting bail 2205 is rocked CCW by the springs 2203 when the shaft 408 is carried rightward, allowing the nine pin sensing levers 2201 to rock to the CCW position with the noses 2217 in the path of the studs 2809. The rack assemblies 300 are blocked thereby in the zero position during a blank cycle, preventing printing of nine in all orders. The printing segments 311 are rocked to subzero positions by a zero suppression mechanism discussed hereinbefore to prevent printing of zeros, as well, so that no value is printed.

Tens carry mechanism

A carry mechanism 3200 (FIG. 32) for performing a tens carry during addition or subtraction operations, including additions and subtractions carried out during multiplication and division, is provided between each numeral wheel 306 (FIG. 3) of the accumulator register 207. Each mechanism 3200 permits a numeral wheel 306 to be driven one tooth space each time the tens carry tooth 1821 on the next lower order wheel 306 rotates from the zero position in which it is shown in FIG. 32 to a nine position 1821-A or from the nine position to the zero position. It will be recalled that during an add cycle, the register 207 is raised into engagement with the upper rack teeth 348 prior to the leftward stroke of the racks 303 and that the numeral wheels 306 are driven CCW during the leftward stroke, adding the value in the racks 303 into the register 207. It will be further recalled that during a minus cycle, the register 207 is lowered into engagement with the lower rack teeth 350 prior to the leftward stroke of the racks 303 and that the numeral wheels 306 are driven CW during the leftward stroke, subtracting the value in the racks 303 from the register 207. In either case, a tens carry is initiated whenever the tooth 1821 is rotated against a live tip 3202 extending from the carry-blocking element 1811, rocking the element CW about the shaft 1813 during addition and CCW during subtraction. When rocked in either direction, the element 1811 is driven against a trip slide 3204, forcing the slide 3204 rightward. An ear 3206 on the right end of the slide 3204 is engaged normally with a shoulder 3208 of a transfer lever 3210, maintaining the lever 3210 in the position shown against the urging of a spring 3212 and a rack carry spring 354 (FIG. 3). Normally, when the main member 301 (FIG. 3) is restored beyond the subzero position as shown in FIG. 3 at the end of a leftward stroke, an ear 3214 extending from the transfer lever 3210 engages a shoulder 3216 on the rack 303 and holds the rack 303 rightward one digit position against the urging of the spring 354 between the main member 301 and the racks 303. However, when the trip slide 3204 (FIG. 32) is driven rightward by the tens carry tooth 1821 of the numeral wheel 306 in the next lower order, the ear 3206 is moved rightward out of engagement with the shoulder 3208, permitting the spring 3212 to rock the transfer lever 3210 CW about a frame shaft 3215. The ear 3214 is carried thereby away from the shoulder 3216 on the rack 303 in the next higher order. When the main member 301 in the next higher order is driven fully leftward, the ear 3214 in the next lower order is 45 CCW permitting the rack 303 to move freely leftward under urging of the spring 354 (FIG. 3). Such leftward movement continues until studs 356 and 358 which extend from the rack 303 into slots 360 and 362 in the main member 301, are against the left edges of the slots. This extra movement of the rack 303 drives the associated numeral wheel 306 an extra tooth space, thereby entering the carry from the next lower order.

At 45° of every cycle, as indicated in line 17A (FIG. 17), a restore bail 3218, extending rightward and leftward beneath all of the transfer levers 3210, is driven by a cam (not shown) in a conventional manner against noses 3220 on the levers 3210. This restore occurs after the accumulator register is centralized. Any levers 3210 that were tripped by a carry during the cycle are driven CCW. The shoulders 3208 cam the ears 3206 and slides 3204 rightward and then disengage from the ears 3206, freeing the slides 3204 for movement leftward under the urging of the springs 3212 to the position shown in FIG. 32 with the ears 3206 beneath the shoulders 3208, latching the levers 3210 in the CCW position.

Total and subtotal credit cycles

Depression of the add-total key 103 (FIGS. 1 and 6) 75 or the subtotal-correction key 105 with no value in the

pin carriage 205 (FIG. 3) releases the respective trip slides 605 and 644 to block the control slide blocking element 1301 (FIG. 13A) in the corresponding position and start a machine cycle in the manner discussed hereinbefore. If the value in the accumulator register 207 is a credit, i.e. negative, then depression of the keys 103 or 105 initiates a total or subtotal cycle which is a credit cycle. During such a cycle the negative value in the accumulator register is printed as a true credit balance.

Whenever a negative value is represented in the accumulator register 207, a credit latch 989 (FIG. 9) is rocked CW in a manner discussed later, carrying an ear 990 extending therefrom to a position 990-A. With the ear 990 in position 990-A, a shoulder 991 formed on a credit slide 992 is opposite the ear. Whenever a positive value is represented in the accumulator register 207, the credit latch 989 is maintained in the position shown in FIG. 9.

Since there is no value in the pin carriage 205 during either a total or a subtotal cycle, the latch 915 is maintained in the position shown so that the total slide 977 is driven leftward with the main slide 913 through engagement of the shoulder 978 on the main slide with the ear on the latch 915. The credit latch 989 is pivoted on the total slide 977 so that as the total slide 977 is driven leftward with the main slide 913, the ear 990 engages the shoulder 991, driving the credit slide 992 leftward also. The slides 901 are blocked in either a total credit position or a subtotal credit position to control the machine to carry out corresponding cycles as follows.

Total credit cycle.—If the add-total key 103 is depressed to initiate a total credit cycle, the control slide blocking element 1301 is in the add-total position 1301-A. Therefore, as the main control slide 913 is driven leftward, the control slides 901 are blocked in a total credit position by engagement of a total credit surface 993 with the element 1301. With the control slides 901 blocked in the total credit position, the vertical slide 918 is in a total credit position 918-H (FIGS. 9 and 16). As indicated in FIG. 16, the ear 954 on the downslide 948 is opposite the notch 1603 and free to be driven rightward; the ear 953, however, is blocked by a solid portion of the vertical slide 918. The mode ball 923 and pins 926 and 1511 are maintained in the position shown so that the hook driver 937 is driven rightward at 40° by the total and subtotal follower 1501 in the manner discussed before. The ear 954 is opposite the notch 1603, while the ear 953 is blocked against a solid portion of the slide 918, preventing rightward movement of the upslide 947. The downslide 948, however, is carried rightward, forcing the downhook 941 into engagement with the stud 964 extending from the accumulator plate 957, rocking the plate CCW and bringing the accumulator register 207 (FIG. 3) downward into engagement with the lower teeth 350 of the racks 303. Consequently, a true credit balance is transferred to the segments 311 during the rightward stroke of the rack assemblies 300, leaving the register 207 zeroized. Other aspects of a total credit cycle are similar to those of a total cycle discussed hereinbefore. In addition to printing the symbol "T" following the value as during a total debit cycle, a — is printed after the T during a total debit cycle in the manner discussed hereinafter.

Subtotal credit cycle.—Depression of the subtotal-correction key 105 with a negative value in the accumulator register 207 and no value in the pin carriage 205 initiates a machine cycle in the manner discussed, during which the control slide blocking element 1301 is positioned in the subtotal-correction position 1301-D. Since there is a negative value in the register 207, the ear 990 on the credit control slide latch 989 is in the position 990-A; and since there is no value in the pin carriage 205, the latch 915 is in the CCW position shown. As the main control slide 913 is driven leftward, the shoulder 978 drives

the latch 915 and the total slide 977 leftward, forcing the ear 990 against the shoulder 991. The slides 901 are driven leftward until a subtotal credit surface 995 is blocked against the control slide blocking element 1301. 5 The vertical slide 918 is driven thereby to the subtotal credit position 918-I (FIGS. 9 and 16), with the ear 953 on the upslide 947 opposite a solid portion of the slide 918 and the ear 954 on the downslide 948 opposite the notch 1605. The mode bail 923 is driven to the subtotal mode position 923-B, the same position to which it is driven during a subtotal cycle discussed before. The hook driver 937 is driven rightward in the manner discussed before, carrying the downslide 948 and downhook 941 rightward into engagement with the stud 964 on the accumulator plate 957, driving the plate 957 and cam 1800 (FIG. 18) CCW. The shaft 310 is driven downward, lowering the accumulator register 207 (FIG. 3) into engagement with the lower rack teeth 350. Consequently, a true credit balance is transferred to the racks 303 and segments 311 and then returned to the register 207. In 10 other respects, a subtotal credit cycle is identical to a subtotal debit cycle. In addition, however, a "—" symbol is printed to the right of the "S" symbol printed during a subtotal debit cycle, such printing being discussed hereinafter.

CREDIT CONTROL MECHANISM

A credit control mechanism 1829 (FIGS. 18, 28 and 33), responsive to positive and negative conditions of 30 the accumulator register 207, is provided to control the position of the credit latch 989 (FIG. 9) and transfer of fugitive digits. The credit latch 989 is maintained in the CCW position whenever the value represented in the accumulator register 207 is positive and is rocked CW, carrying the ear 990 to the position 990-A, whenever the value represented in the accumulator register 207 is negative. The position of the latch 989, which corresponds to the sign of the value represented in the register 207, determines the position in which the control slides 901 35 are stopped and whether a total or subtotal cycle is carried out as a debit or credit cycle such as discussed in the preceding sections. The second function of the credit control mechanism 1829 is the addition or subtraction into the lowest order numeral wheel 306 of the accumulator register 207 of a fugitive digit at appropriate times and the 40 blocking of a fugitive digit at other times.

Control of credit latch

With the accumulator register 207 in a positive condition, the credit latch 989 (FIGS. 9 and 28) is held in 50 the CCW position in which it is shown by a credit lever 2821. A credit link 2823 connects the credit lever 2821 to a credit bellcrank 2825 keyed to a credit shaft 2827. The shaft 2827 is maintained in the position shown as long as a positive value is in the accumulator register; the 55 credit link 2822 maintains the credit lever 2821 and credit latch 989 thereby in the CCW positions.

In order for the accumulator register 205 to be in a credit or negative condition, a minus or subtraction cycle must be carried out during which the tens carry tooth 60 1821 (FIG. 18) extending from the left most or highest order accumulator numeral wheel 306 is rocked CW from the zero position in which it is shown to the nine position 1821-A (FIG. 3). It will be recalled from a preceding discussion that during a minus cycle the box cam 65 1800 (FIG. 18) is rocked CCW forcing the shaft 310 and the accumulator register numeral wheels 306 downward into engagement with the lower rack teeth 350. A fugitive digit box cam 1831 is freely mounted on the shaft 1802 and is provided with a cam slot 1832 which is engaged 70 with the accumulator register shaft 310. The cam 1831 is cammed CCW when the shaft 310 is driven downward by the accumulator register box cam 1800 during a minus cycle. A fugitive digit link 1834 which is pivoted to the 75 fugitive digit box cam 1831, is carried upward and left-

ward with the cam 1831, when the cam is rocked CCW. A slot 1835 in the fugitive digit link 1834 is in engagement with a stud 1837 extending from a driving lever 1839 which is pivoted at 1840 on a special highest order carry lever 1841. As the fugitive digit link 1834 is driven upwards and leftwards by the cam 1831, the driving lever 1839 is rocked CW about the pivot 1840 to a position in which a credit nose 1843 is in a position 1843-A opposite a credit stud 1845 extending from a lever 1847. The lever 1847 is keyed to the credit shaft 2827 and is shown in a debit position corresponding to a debit condition in the accumulator register 207.

Since the shaft 310 is driven downward during a minus cycle, the credit nose 1843 is rocked CW by the link 1834 to the position 1843-A, opposite the credit stud 1845. When the register 207 is placed in a minus condition by subtractive entries, the register 207 changes from a positive to a negative condition. The tens carry tooth 1821 on the highest order accumulator gear 306 is driven from the zero position to the nine position 1821-A in a CW direction, rocking the carry blocking element 1811 CCW about the shaft 1813, driving the trip slide 3204 rightward and releasing the special highest order carry lever 1841 for CW movement about the carry lever shaft 3215 under the urging of a spring 1849 and a fugitive digit carry spring 1890. Clockwise movement of the highest order carry lever 1841 forces the credit nose 1843 against the credit stud 1845, forcing the stud 1845 to a credit position 1845-A and the lever 1847 CW to a credit position. The credit bellcrank 2825 (FIG. 28), being keyed to the credit shaft 2827 with the lever 1847, is driven CW, forcing the credit link 2823 rightward. The ear 990 (FIG. 9) is rocked CW thereby to the position 990-A for engagement with the shoulder 991 on the credit slide 992. With the ear 990 so positioned either total or subtotal credit cycles may be carried out in the manner discussed hereinbefore.

Subsequent add cycles carried out after the lever 1847 is driven to the credit position may cause the register 207 to go to a positive condition. As discussed hereinbefore, the accumulator box cam 1800 is driven CW during an add cycle, raising the shaft 310 and carrying the accumulator register 207 into engagement with the upper rack teeth 348. The fugitive digit box cam 1831 (FIG. 18) is driven rightward by the rising shaft 310, forcing the fugitive digit link 1834 rightward and downward. The driving lever 1839 is rocked CCW thereby, about the pivot 1840, to a position in which a debit nose 1851 is in a position 1851-A opposite a debit stud 1853 extending from the lever 1847. Since the lever 1847 is in the CW credit position from the previous subtraction, the debit stud 1853 is in a credit position 1853-A opposite the debit nose 1851 prior to such rocking. As the accumulator register is driven from the negative condition to a positive condition during the add cycle, the tens carry tooth 1821 on the highest order numeral wheel 306 is driven CCW from the nine position 1821-A to the zero position. The special highest order carry lever 1841 is released thereby to rock CW about the carry lever shaft 3215, forcing the debit nose 1851 downward against the debit stud 1853, driving the stud 1853 to the CCW debit position. The lever 1847 and credit shaft 2827 are rocked CCW thereby driving the credit bellcrank 2825 (FIG. 28) CCW. The credit link 2823 is forced leftward, driving the credit latch 989 CCW to the debit position with the ear 990 clear of the shoulder 991 (FIG. 9). A total or subtotal cycle initiated with the ear 990 away from the shoulder 991 results in a debit total or subtotal cycle in the manner discussed hereinbefore.

Fugitive digit transfer

In order to print a true negative balance contained in the accumulator register 207, a fugitive digit is subtracted from the lowest order numeral wheel 306 of the accumulator register 207 whenever the register 207 goes from a

positive to negative condition, i.e. when the highest order numeral wheel tens carry tooth 1821 (FIG. 18) is moved CW from the position shown to the position 1821-A. Alternatively, when the register 207 goes from a negative condition to a positive condition during an add cycle, a fugitive digit is added into the lowest order numeral wheel 306 after the highest order numeral wheel 306 passes from the position 1821-A to the positive zero position.

To carry out such additions and subtractions of fugitive digits, a first order trip cam 3301 (FIG. 33) is keyed to the credit shaft 2827. The cam 3301 is rocked with the lever 1847 (FIG. 18) each time the accumulator register 207 passes from a positive condition to a negative condition or a negative condition to a positive condition. The upper end of the trip cam 3301 (FIG. 33) is engaged with a roller 3303 on a fugitive digit bellcrank 3305. Each time the credit shaft 2827 is rocked CW from the debit position in which it is shown to the credit position, the trip cam 3301 moves from the debit position in which it is shown, to a credit position 3301-A. Such movement rocks the fugitive digit bellcrank 3305 CW. Similarly, rocking of the credit shaft 2827 and the cam 3301 CCW from the credit position to the debit position again drives the fugitive digit bellcrank 3305 CW. Each time that the fugitive digit bellcrank 3305 is rocked CW, a stud 3307 extending from a first order trip slide 3309 which is associated with the lowest order numeral wheel 306, is engaged by the bellcrank, driving the trip slide 3309 rightward. As the ear 3206 moves from beneath the shoulder 3208, the transfer lever 3210, associated with the first order, rocks CW. The ear 3214 is rocked away from the shoulder 3216 (FIG. 32) on the first order rack 303, permitting the rack to move one additional tooth space leftward, entering a fugitive digit into the lowest order numeral wheel 306 of the register 207. If the bellcrank 3305 is rocked during a minus cycle, during which the accumulator register 207 is in engagement with the lower rack teeth 305, the digit is subtracted from the lowest order numeral wheel 306. If the fugitive digit bellcrank 3301 is rocked CCW during an add cycle, during which the accumulator register 207 is in engagement with the upper rack teeth 348, leftward movement of the lowest order rack 303 adds a fugitive digit to the lowest order to accumulator wheel 306.

DIVIDEND TAB KEY AND TAB STOP LEVER

As discussed in the General Description, the dividend tab key 120 (FIG. 1) and the tab stop lever 122 are provided for positioning the pin carriage 205, after entry of a dividend value therein, in either a partial or full tab position in order to obtain larger quotient values. After such positioning, depression of the add-total key 103 initiates an add cycle during which the dividend value, represented in the pin carriage 205, is entered into higher orders of the accumulator register 207.

Prior to entry of the dividend value into the pin carriage 205 (FIG. 23), the cleared carriage 205 stands in the position shown in FIG. 23 with the highest order row of pins 304-Z aligned with the fourth order rack assembly 300. Depression of any value key 101 (FIG. 1) detents a corresponding value pin 304 (FIG. 23) into the path of a shoulder 305 (FIG. 3) and releases the pin carriage 205 for escapement leftward one order, in the manner discussed under "Pin Carriage Escapement". Such escapement brings the detented pin 304 into the path of the shoulder 305 of the next higher order rack assembly 300. After entry of a complete dividend value, and order by order escapement of the pin carriage 205, the value may be entered into the orders of the accumulator register 207, opposite the detented pins 304, by depression of the add-total key 103. In order to obtain larger quotient values, however, the dividend tab key 120 and the tab stop lever 122 may be used to partially tab the pin carriage 205 to a position in which the highest order pins

304-Z are opposite an intermediate rack assembly such as assembly 300-I and a corresponding order of the accumulator register 207. Alternatively, the keys 120 and 122 may be used to tab the pin carriage fully leftward to a position in which the pins 304-Z are opposite the leftmost or highest order of the accumulator register 207.

Partial tab

With the tab stop lever 122 (FIGS. 1, 19 and 19A) in the partial tab or rightward position, the position shown, depression of the dividend tab key 120 results in escapement of the pin carriage 205 to line up the pins 304-Z (FIG. 23) with the intermediate rack assembly 300-I. Depression of the dividend tab key 120 forces a depending lever 1902 CCW about a frame shaft against a spring 1903. This drives a live tip 1904, which is pivoted on a stud 1905 extending from the lever 1902, against a frame member 1906, rocking the live tip 1904 CW about the stud 1905. A driving nose 1907 is forced against a nose 1909 formed on the nine pin stop 1901. The stop 1901 is mounted on a frame shaft 1911 and is spring urged CW about the shaft by a spring 1913. Engagement of the nose 1907 with the nose 1909 rocks the nine pin stop 1901 CCW, moving the stop 1901 out of the path of the nine pins 304-9, thereby freeing the pin carriage 205 for movement leftward.

A stud 1915 extends from a tab stop 1917. Stop 1917 is guided in frame members 1906 and 1919 and is urged by a spring 1921 into engagement with a forward extending projection 1923 of the dividend tab key lever 1902. Depression of the dividend tab key 120 releases the tab stop 1917 to be spring urged downward. An ear 1927 extending from the tab stop 1917 is lowered to a position 1927-A in the path of a projection 1925 (FIGS. 19, 19A and 23) extending upwards from the pin carriage 205. Consequently, with the lever 122 in the rightmost or partial tab position, the stud 1915 is free to move downward into the path of the projection 1925. Depression of the dividend tab key 120 cams the nine pin stop away from the nine pins 304-9, releasing the pin carriage for movement leftward until the projection 1925 is blocked against the ear 1927 at the intermediate position.

Full tab

With the tabulator stop slide lever 122 in the full tab or a leftmost position 122-A, depression of the dividend tab key 120 disengages the nine pin stop 1901 from the nine pins 304-9, permitting escapement of the pin carriage 205 fully leftward to a position in which a bushing 2305 (FIG. 23) engages a bushing 2307 which is mounted around a pin carriage guide shaft 2309 and against a left frame member 2311. With the tab stop lever 122 in the full tab position 122-A a hook 1929, which extends from the lever 122, is beneath the stud 1915. Consequently, the hook 1929 prevents the tab stop 1917 from being lowered into the path of the projection 1925. This permits the projection 1925 to pass beneath the tab stop ear 1927 and the pin carriage 205 to escape fully leftward, to a position with the bumper 2305 against the bushing 2307.

KEYBOARD INTERLOCKING

Keyboard interlocking is provided between the adding machine keys 201, the multiplication-division control keys 203, the value keys 101 and the dividend tab key 120 to prevent operator errors and jamming of the machine.

Adding machine keys interlocking

The interlocking is arranged so that depression of any one of the adding machine keys 201 including the add-total key 103, the repeat add key 104, the subtotal-correction key 105, and the nonadd key 109 blocks the dividend tab key 120, the value keys 101 and the multiplication-division control keys 201 from depression. Another feature of the interlocking provides that depression of a sec-

ond adding machine key 201 after depression of the first key will have no effect. Depression of the first key 201 releases a corresponding trip slide (FIG. 6) to rock the clutch starting bail 703 (FIG. 7) and initiate an operation. Upon depression of the second key, the corresponding trip slide (FIG. 6) idly moves forward against the already tripped clutch starting bail 703 or the slide 1001 (FIG. 10).

Generally, depression of the first adding machine key 201, releases the corresponding trip slide for movement forward to rock the bails 703 (FIGS. 7, 11 and 34) and 1103 CCW. Counterclockwise rocking of the bail 703 (FIG. 34), brings the bail into engagement with a forward ear 2005 (FIGS. 11, 20 and 34) of an escapement interlock latch 2007. The escapement interlock latch 2007 is pivoted at 2009 on the forward end of an interlock bar 2011. The bar 2011 has forward and rearward slots 2012 and 2013 which are guided by studs 2015 and 2016 which extend upward from the frame. The bar 2011 is urged forward by a spring 2018 which is between the frame stud 2015 and a stud 2041 extending upward from the bar 2011. The escapement interlock latch 2007 normally is held by a spring 2019 between the latch and the bar 2011 in the CW position shown, engaged with an ear 2021 extending upwards from a restore link 2023 which is also guided by studs 2015 and 2016. The link 2023 normally is held in the position shown. With the latch 2007 engaged with the ear 2021, the interlock bar 2011 is restrained from moving forward under urging of the spring 2018.

Engagement of the shaft 701 with the ear 2005 (FIGS. 20 and 34) rocks the latch 2007 CCW about the pivot 2009, out of engagement with the ear 2021. This permits the interlock bar 2011 to move forward under the urging of the spring 2018.

Forward movement of the interlock bar 2011, in response to depression of a key 201, blocks the dividend tab key 120, the value keys 101 and the multiplication-division control keys 203 from depression by the following means.

Dividend tab key blocked.—With the interlock bar 2011 (FIGS. 19, 19A and 20) in the forward position, an ear 1931, which extends upward from an arm 1933 on the bar 2011, is in a position 1931-A beneath the stud 1905 on the dividend tab key lever 1902. The dividend tab key 120 is interlocked thereby from depression during any cycle initiated by an adding machine control key 201, preventing escapement of the pin carriage 205 in response to depression of the key 120 during the cycle. If such interlocking were not provided, a rack assembly 300 in the rightward position being returned leftward could drive the projection 305 on the main member 301 (FIG. 22) against a depressed value pin 304 which was shifted to the left of the projection, during the interval that the rack assemblies were rightward, possibly jamming or splitting the pins 304.

Value keys blocked.—With the interlock bar 2011 in a forward position as a result of depression of one of the adding machine control keys 201, ears 2025 and 2027 (FIG. 20) extending upward from the interlock bar are positioned beneath arms 2001 and 2002 of the escapement 60 bail 2003. Since a shoulder 2103 (FIG. 21) extends from each value key 101 over the escapement shaft 2105 which is carried in the escapement bail 2003, all value keys 101 are blocked from depression, preventing jamming or a further value entry into the pin carriage 205 after initiation of a machine cycle.

Multiplication-division control keys blocked.—In response to depression of one of the adding machine control keys 201, the bails 703 and 1103 (FIG. 7) are rocked CCW. An arm 3501 (FIGS. 35 and 36) is suitably fastened to the bail 1103 and is carried CCW with the bail. A stud 3503 extends from the arm 3501 into a slot 3505 formed in an interlock bellcrank 3507, forcing the bellcrank CW about a frameshaft. A stud 3509 extends upwards from the bellcrank 3507 into engagement with a

slot in an interlock bar 3511, driving the bar rightward when the bellcrank 3507 is rocked CW. Forward ends of a divide key lever 3513 and a multiplier key lever 3515, depending respectively from the divided key 118 and the multiplier entry key 110, are formed with slots 3517 and 3519 adjacent shoulders 3521 and 3523 on the interlock bar 3511. Movement of the interlock bar rightward brings the respective shoulders into engagement with the slots 3521 and 3523 and thereby locks the multiplier entry key 110 and division key 118 from depression. Depression of the total = key 112, subtotal = key 114 or negative = key 116 is ineffectual unless the multiplier entry key 110 is first depressed. Blocking of the keys 112, 114 and 116 is therefore not necessary after depression of an adding machine control key 201.

Multiplication-division control keys interlocking

Depression of a multiplication-division control key 203 including the multiplier entry key 110, the total = key 112, the subtotal = key 114, the negative = key 116 or the divide key 118 renders depression of any of the adding machine control keys 201 ineffective and blocks depression of the value keys 101 and the dividend tab key 120.

Adding machine control keys ineffectual.—In order to render the adding machine control keys 201 ineffectual upon depression of a key 203, the forward edge of the lever 3515 (FIG. 35), which lever depends from the multiplier entry key 110, is lowered into the path of the shoulder 3523 of the interlock bar 3511 whenever the key 110 is depressed. Although, any of the adding machine keys 201 can be depressed, such blocking renders the depression ineffective since the clutch starting bail 703 is prevented by the bellcrank 3507 from rocking CCW. Similarly, depression of the division key lowers the forward edge of the divide key lever 3513 into the left shoulder 3221 of the interlock bar 3511, blocking rightward movement of the bar 3511 whenever the key 118 is depressed, preventing rocking of the bail 703.

Dividend tab key blocked.—During any part of a multiplication or division operation, the dividend tab key 120 is blocked from depression. Depression of any key 203, initiates movement of a master program plate 3401 (FIG. 34), leftward from the position shown to start a machine cycle in a manner discussed hereinafter. During such leftward movement, a right finger 3403 extending from the plate 3401 is forced against a stud 1108 (FIGS. 11 and 34) which extends from an arm 1110 that is pinned to the shaft 705. The shaft 705 is driven CCW thereby (FIG. 34). An interlock bail 1112, also pinned to the shaft 705, is rocked CCW against the escapement interlock latch 2007 (FIGS. 20 and 34) upon leftward movement of the master plate, rocking the latch 2007 CCW out of engagement with the ear 2021 in the manner discussed hereinbefore, permitting the spring 2018 to move the interlock bar 2011 forward. With the interlock bar forward, the upward extending ear 1931 (FIGS. 19 and 19A) blocks depression of the dividend tab key 120 and the depending lever 1902.

Value keys blocked.—The value keys 101 are also blocked after depression of a key 203. The master plate 3401 is moved leftward releasing the interlock bar 2011 for movement forward when a key 203 is depressed as discussed above. The value keys 101 are blocked from depression, by movement of the interlock bar ears 2025 (FIG. 20) and 2027, beneath the escapement bail arms 2001 and 2002. The shaft 2105, which is carried by the arms, blocks all keys 201 in the manner discussed before.

Value keys interlocking

Simultaneous depression of a value key 101 and either an adding machine control key 201 or a multiplication-division control key 203 prevents the depressed control key from starting a cycle of operation until the depressed value key is released. Depression of a value key 101 rocks

the bail 2003 (FIG. 21) CW, bringing the arms 2001 and 2002 of the bail into the path of the ears 2025 and 2027 extending upward from the interlock bar 2011. The interlock bar 2011 is blocked thereby from moving forward even though the escapement interlock latch 2007 is released by depression of a control key 201 or 203. The bails 703 and 1103 are prevented from rocking CCW (FIG. 7) to start the machine until the bail 2003 is raised by release of a key 201, to permit the slide 2011 to move completely forward to release the slide 1001 for movement leftward.

Adding machine control keys ineffectual.—First, depression of an adding machine control key 201 simultaneously with a value key 101 releases a corresponding trip slide (FIG. 6) for movement forward against the shaft 701 (FIG. 7) in an attempt to rock the bail 703 forward to start the machine cycle and release the keyboard sensing slide 1001 (FIG. 10) in the manner discussed hereinafter. However, with a value key 101 and a control key 201 depressed simultaneously, the escapement bail arms 2001 and 2002 block the interlock bar ears 2025 and 2027. The interlock bar 2011 therefore cannot be substantially driven from the position indicated in FIG. 20 when the master plate 3401 (FIG. 34) is moved leftward in response to depression of a control key 203. Consequently, as the shaft 701 is rocked against the ear 2005, driving the latch 2007 CCW out of engagement with the ear 2021, the shaft 701 also engages a forward ear 2029, extending downward from the interlock bar 2011, and is blocked from further movement as long as the interlock bar 2011 is restrained by the escapement bail arms 2001 and 2003. The clutch starting bail 703 is prevented thereby from rotation to a position which starts the motor or releases the keyboard sensing slide 1001. Upon release of the value key 101, the escapement bail arms 2001 and 2003 are permitted to rise out of engagement with the interlock bar ears 2025 and 2027, releasing the bar and permitting the clutch starting bail 703 to be driven to its full CCW position to initiate the cycle.

Multiplication-division control keys blocked.—Second, depression of a value key 101 simultaneously with a multiplication-division key 203 prevents effective depression of another key 203. Depression of a key 101 brings the arms 2001 and 2002 of the escapement bail 2003 (FIG. 20) into the path of the ears 2025 and 2027 extending upward from the interlock bar 2011, blocking the bar from movement forward. Depression of any key 203, when activated by prior depression of the multiplier entry key 110, releases the master plate 3401 (FIG. 34) to move leftward, bringing the right finger 3403, extending from the master plate, into engagement with the stud 1108 (FIGS. 11 and 34) on the arm 1110 on the shaft 705. The shaft 705 is rocked CCW thereby, carrying the interlock bail 1112 (FIG. 34) into engagement with the forward ear 2029 (FIGS. 20 and 34) that extends downward from the interlock bar 2011 and is blocked in that position from further CCW rotation. With the finger 3403 in engagement with the stud 1108, the master plate 3401 is held from moving fully leftward and starting a machine cycle. Upon release of the value key 101 the escapement bail arms 2001 and 2002 rise out of the path of the ears 2025 and 2027, permitting the bar 2011 to move fully forward. This movement permits the interlock bail 1112 to be driven CCW by the finger 3403 on the master plate 3401, and the master plate to move fully leftward to initiate the operation.

Dividend tab key

Depression of the dividend tab key 120 (FIG. 19A) renders ineffective the depression of any control key 201 or 203. With the dividend tab key lever 1902 lowered, the stud 1905, which extends from the lever 1902, is in a position forward the upper extending ear 1931 on the arm 1933 of the interlock bar 2011. The interlock bar

2011 (FIGS. 19, 19A and 34) is blocked thereby from full movement forward. The interlock bar 2011 in turn blocks the shaft 701 and the clutch starting bails 703 and 1103 from being fully rocked by a trip slide upon depression of an adding machine control key 201. The interlock bar 2011 also blocks the interlock bail 1112 upon depression of a key 203 to prevent a machine cycle from being initiated. Release of the dividend tab key lever 1902 frees the interlock bar 2011 to move forward and permit either the clutch starting bails 703 and 1103 or the master plate 3401 to move to a position to initiate the machine cycle.

RIBBON CONTROL MECHANISM

During every machine cycle, an inked ribbon 329 (FIGS. 3 and 37) that comprises a black section 329-B and a red section 329-R is shifted to a position in which one of those sections is along a line of pressure between the platen 327 and the printing segments 311. The platen 327, however, is rocked for printing against the tape 328, ribbon 329 and segment 311 only during predetermined cycles.

Table I indicates during which cycles the values and symbols are printed in red. Other values and symbols not shown in Table I are either positive or negative listings and are printed in black. Generally, all listings are printed in black and all totals are printed in red.

TABLE I.—CYCLES DURING WHICH VALUES ARE PRINTED IN RED

Cycle:	Red symbols
Total debit	T
Total credit	T
Subtotal debit	S
Subtotal credit	S
Transfer of multiplier value from the accumulator register to the multiplier register	X
Print product:	
Positive total	T
Negative total	T
Positive subtotal	S
Negative subtotal	S
Print remainder	RM
Print quotient	Q

The inked ribbon 329 is wrapped on a spool 3701 (FIG. 37) which is mounted on a stud 3703 extending from a ribbon box 3705. The spool 3701, ribbon 329 and box 3705 are mounted to the right of the printing segments 311 (FIG. 3). A similar spool, ribbon and box (not shown) are mounted to receive the ribbon on the other side of the printing segments 311. The ribbon 329 is transferred from one spool 3701 to another in a well-known manner not forming part of this invention nor herein disclosed.

Print black

The ribbon boxes 3705 are pivoted on reduced ends of the shaft 324 and are normally held in the positions shown by other reduced ends 3707 of the shaft 326 in engagement with camming surfaces 3709 which extend upward from the boxes 3705. Right and left ribbon control links 3711 are pivoted to respective right and left ribbon boxes 3705 at points 3713. Right and left springs 3715 between the links 3711 and the machine frame urge the boxes 3705 CCW about shaft 324.

During every cycle the shaft 326 is carried from the position shown to the position 326-A as discussed before. The reduced ends 3707 are moved out of engagement with the ribbon box camming surfaces 3709, releasing the boxes 3705 and ribbon 329 to move CCW under the urging of the springs 3715. Pivoted to the lower end of the ribbon control links 3711 are right and left arms 3717 of a ribbon control bail 3719. As the ribbon control links 3711 are urged upward, the arms 3717 are rocked CW about a frame shaft 3721, bringing a shoulder 3722

on the left arm 3717 into engagement with a stud 3723 that extends from a ribbon control slide 3725 which is normally in the position shown. The ribbon control links 3711 drive the ribbon boxes 3705 CCW thereby to a print black position 3705-B so that the section of black ribbon 329-B is positioned along the line of pressure between the platen 327 and the printing segments 311 for printing the values represented by the segments 311 in black.

Print red

It is noted that in Table I all of the cycles during which the values and symbols are printed in red, are cycles during which no value is in the pin carriage. The values printed are from the accumulator register except the value printed during a print quotient cycle. Since there is no value in the pin carriage during these cycles, the total power link 2805 (FIG. 28) remains in engaging relation with the stud 2809, driving the stud 2809 rightward during these cycles. It will be recalled that rightward movement of the stud 2809 drives the total box cam 1823 (FIG. 18) CW by means of the link 2907 (FIG. 29), forcing the rear trip slide support shaft 1827 leftward. The shaft 1827 extends rightward into engagement with a ribbon control lever 3727 (FIG. 37) and normally maintains the lever in the position shown against the urging of a spring 3729. The ribbon control slide 3725 is slidably mounted on a frame shaft 3731 and is pivoted to the ribbon control lever 3727. The slide 3725 is normally maintained by the lever in the leftward position shown in FIG. 37. However, during all of the cycles indicated in Table I, the total power link 2805 (FIG. 28) drives the stud 2809 rightward, driving the arms 2901 and 2905 (FIG. 29) CW, the link 2907 leftward, and the cam 1823 (FIG. 18) CW. The rear trip slide support shaft 1827 (FIGS. 18 and 37) is cammed leftward thereby. The ribbon control lever 3727 is rocked CW about a frame shaft 3733 and the ribbon control slide 3725 driven rightwards, carrying the stud 3723 to a position 3723-A in which the stud 3723 is clear of the shoulder 3722 on the right arm of the ribbon control 3719. Consequently, when the shaft 326 (FIG. 37) is moved CCW, carrying the reduced end 3707 away from the camming surface 3709, the ribbon box moves to a print red position 3705-R. The box 3705 is stopped in this position by engagement of the right arm 3717 with the stud 3723, positioning the red ribbon section 329-R along the line of pressure between the segments 311 and the platen 327, to print in red the value represented by the printing segments 311.

MINUS SYMBOL PRINTING

A minus symbol segment 3739 (FIG. 37) is provided to print a minus symbol during certain cycles. After rotation of the segment 3739 to a print position, impression of the minus symbol is made by a rightward edge 3741 of an ear 3743 which is formed on the segment.

A minus symbol control link 3745 is pivoted at 3747 to the minus symbol segment 3739. A spring 3749, connected between a frame shaft 3751 and a stud 3753 extending from the minus symbol control link 3745, urges the link upward and the minus symbol segment CCW. Counterclockwise driving of the shaft 326 (FIGS. 3, 4 and 37), by means discussed in the Edward's application referred to hereinbefore, releases the minus symbol segment 3739 to rock CCW under the urging of the spring 3749. The minus symbol segment 3739, however, is blocked with the edge 3741 in either a nonprint position 3741-A or a print position 3741-B by the following means. A stud 3755, which extends from the lower end of the minus symbol control link 3745, is engaged in a camming slot 3757 in a minus symbol control slide 3759. Upward movement of the minus symbol control link 3745 cams the minus symbol control slide 3759 leftward to either a corresponding nonprint or print position.

The minus symbol control slide 3759 can be blocked in the nonprint position by either the segment 1323 or the symbol step plate 3003 (FIGS. 13A and 30).

Segment blocking

The segment 1323 is keyed to the shaft 1321 and is maintained in a position corresponding to the position of the main control slide 913 (FIG. 9). It will be recalled from the "Adding Machine Keys and Mechanism" section that the vertical slide 918 is driven to the positions 918-A-I during various cycles and the slide 913 to corresponding positions. The arm 1319, which is keyed to the shaft 1321, is held by a spring 3765 against the stud 1317 that extends from the main slide 913. As the slide 913 is driven leftward and the slide 918 upward to be blocked in one of the positions 918 A-I, the arm 1319 rocks the shaft 1321 and the segment 1323 CCW to a corresponding position from the "home" position shown in FIG. 37. The positions of the segment 1323 are indexed with respect to a blocking ear 3768 extending downward from the minus symbol control slide 3759. As the slide 3759 is cammed leftward, the ear 3768 is blocked either against the outer edge of the segment or against the inner edge of a total minus notch 3761-A, a subtotal minus notch 3761-B, a nonadd notch 3761-C, or a minus notch 3761-D, depending on the position to which the slide 913 is driven. With the minus symbol control slide ear 3768 blocked against the outer edge of the segment 1323, the edge 3741 is moved to the nonprint position 3741-A. When the minus symbol control ear is against the inner edge of one of the notches 3761-A-D, the edge 3741 rises to the print position 3741-B.

Symbol step plate blocking

The symbol step plate 3003 (FIGS. 30, 30A and 37) is also used to block the minus symbol control slide 3759 or allow it to pass leftward. The edge 3741 is rocked correspondingly to the position 3741-A or 3741-B. Three holes 3013, 3014 and 3015 are formed along a rear edge 3017 of the plate 3003. A projection 3019 that extends from the left end of the minus symbol control slide 3759 may be blocked against the rear edge 3017 or pass through one of the holes 3013, 3014, or 3015, depending upon the position of the plate 3003. It will be recalled from the discussion under "Add Total Key, Total Debit Function" that the symbol step plate 3003 is positioned, with respect to the symbol rack 3001, according to the position in which the keyboard sensing slide 1001 (FIG. 13) is blocked when an adding machine control key 201 is depressed. The symbol plate 3003 is positioned by other means, discussed hereinafter, during multiplication and division printing operations.

In positions of the symbol step plate 3003 which permit the projection 3019 to pass through one of the holes 3013, 3014, 3015, the projection is shown through the edge 3017 in dotted outline in FIG. 30. In the positions at which the projection 3019 is blocked, the projection 3019 is shown in dotted outline against the rearward edge of the plate 3017. The positions to which the symbol step plate 3003 may be driven are indicated by the symbol opposite respective positions. The symbols and positions correspond to the symbols indicated on the steps.

In order for the minus symbol control slide 3759 (FIG. 37) to move fully leftward to the position which permits the edge 3741 to rise to the print position, 3741-B, one of the notches 3761-A-D in the symbol sector 3761 must be opposite the blocking ear 3768, and one of the holes 3013, 3014 or 3015 in the rearward edge of the symbol step plate 3003 must be opposite the projection 3759. The combination of positions of the symbol step plate 3003 and the segment 1323 which block or pass the minus symbol control slide is summarized in Table II.

TABLE II.—SYMBOL PLATE AND SEGMENT POSITIONS IN WHICH THE MINUS SYMBOL CONTROL SLIDE IS PASSED OR BLOCKED TO PRINT OR NOT PRINT THE MINUS SYMBOL

5	Symbol Plate 3003		Segment 1323		Minus Symbol Control Slide 3759	Minus Printed by Edge 3741

PLATEN CONTROLS, PRINTING AND PAPER ADVANCE

25 Platen controls (FIGS. 31, 38, 38A, 38B and 38C) are provided to print and to selectively advance the tape 328 in single, double, and triple spaces between lines of printing, and when printing is not called for, to not advance the paper tape 328. Generally, printing is carried out by forcing the platen 327 (FIGS. 1, 3, 31 and 38A) and the paper tape 328 to a position 327-A against the ribbon 329 and printing segments 311. The tape 328 is tightly held to the platen, in a well known manner not disclosed herein, and carried by the platen to all positions of the platen. After printing, the platen 327 is invariably fed four spaces CW, carrying a line of printing 3809 on the paper tape 328 from the printing position along the line of pressure 3811 to a viewing position 3809-A. If a new line of printing is to be printed a single space below the preceding line during the next printing operation, the platen 327 and paper tape 328 are back spaced three spaces to a printing position. If a new line of printing is to be two spaces below the preceding line, the platen 327 and paper tape 328 are back spaced two spaces to a printing position. 30 If a triple space is required between lines of printing, then the platen and paper tape are back spaced one space to a printing position. During operations which do not call for printing, the platen is maintained in a stationary position with no paper advance.

Printing

35 During cycles which call for printing, the platen 327 and paper tape 328 are first rocked leftward by complementary cams 3127 and 3129 (FIG. 31), against the ribbon 329 (FIG. 3) and value and/or symbol representing printing segments 311 to print the values and/or symbols. The platen is then returned rightward by the cams to the original position. A second pair of complementary cams are provided on the other side of the platen but are not shown. Generally, the mechanism of FIG. 31 is provided with corresponding members on the opposite side of the platen but are not shown and are not usually referred to hereinafter. Such rocking by the cams 3127 and 3129 is enabled when the enabling lever 3111 is rocked to the CCW position by means discussed hereinbefore and other means discussed hereinafter. The left bifurcated arm of the enabling lever 3111 carries the stud 3113 which extends from the enabling latch 3115, which latch is pivoted at 3121 on the print lever 3123. Counterclockwise rotation of the enabling lever 3111 carries the stud 3113 downward into engagement with a notch 3117 formed in the print cam follower 3119. The complementary cams 3127 and 3129 are keyed to the main shaft 330 and drive the follower 3119 first CCW and then CW each machine cycle.

according to the curve indicated on line 5C (FIG. 5). If the stud 3113 is not carried into the notch 3117, the rocking of the print cam follower 3119 is idle and has no effect upon the platen 327; however, with the stud 3113 in engagement with the notch 3117, the print cam follower 3119 is driven against the stud 3113, forcing the print lever 3123 CCW about the shaft 3125. A stud 3131 extending from a printer arm 3133 is engaged in a slot 3135 in the upper end of the print lever 3123. The platen 327 is mounted on a platen shaft 3137 which is mounted in a printer frame 3138. The printer frame is pivoted on the shaft 3125 by means of right and left arms, only the left being shown. A printer toggle arm 3139 is mounted on each end of the platen shaft 3137. A stud 3141 extends from each of the toggle arms 3139 into engagement with holes formed in the printer arms 3133. As the cams 3127 and 3129 rotate CW, the follower 3119 first is rocked CCW, driving the print lever 3123 CCW through engagement with the stud 3113. The printer arm 3133 is driven CCW about the shaft 324 (FIGS. 3 and 31) driving the toggle arm 3139 CCW about the shaft 3137, forcing the stud 3141 to the position 3141-A. The shaft 3137, platen 327 and printer frame 3138 are driven CCW about the shaft 3125, toggling the platen 327 and tape 328 to the printing position 327-A, firmly against the printing segments 311 and an inked ribbon to carry out printing. When driven by the print lever 3123 to the printing position, the printer arm 3133 and toggle arm 3139 create large forces between the platen 327 and segments 311, clearly imprinting the values and symbols on the tape 328.

Single space printing

In order to print a line in a blank space that is located a single space beneath the line in position 3809-A (FIG. 38A), the platen 327 is backspaced three spaces as the platen is driven to the position 327-A, bringing the line 3809-A to a position 3809-B. A blank space that is a single space beneath position 3809-B is normally in a position 3809-1, but after backspacing the space lies along the line of pressure 3811.

At the beginning of a machine cycle, prior to rocking the platen 327 leftward against the segments 311, a pawl driver cam 3813 (FIG. 38B) that is keyed to the shaft 330 is driven CCW thereby. A follower 3815, which extends from a pawl driver 3817 that is slidably mounted on shafts 330 and 3125, rides on the surface of the cam 3813. A roller 3819 is pivoted on a locking pawl 3821 which is slidably mounted on studs 3823 and 3825. The roller 3819 rides on an upper surface of the pawl driver 3817. A spring 3827 is connected between an ear 3829 on the locking pawl 3821 and the shaft 3125. The roller 3819 is forced thereby against the pawl driver 3817 which in turn forces the stud 3815 against the pawl driver cam 3813. The fall and rise of the cam 3813 during every machine cycle is indicated on line 39A (FIG. 39). At 60° of a cycle, the surface of the cam 3813 that is opposite the stud 3815 falls, permitting the spring 3827 to force the locking pawl 3821 and pawl driver 3817 downward. The locking pawl, however, is blocked from full downward movement by engagement of the ear 3829 with a surface 3831 of a shroud 3833 (FIG. 38C). The shroud is mounted on the shaft 3125 and is urged CW by a spring 3835 which is connected to a stud 3837 extending from the shroud. The stud 3837 is blocked against a double space hook 3839 more fully discussed hereinafter, preventing the shroud from CW rotation. Referring to line 39A (FIG. 39), at 80° of the machine cycle, the pawl driver cam 3813 falls to the lowest point, permitting the driver 3817 and pawl 3821 to drop. The ear 3829 is urged against the shroud surface 3831 and prevented thereby from falling into a tooth space of a spacing gear 3841 which is mounted on the shaft 3125.

Also, at 80°, line 39B (FIG. 39), of a machine cycle, a pair of pawl rocker complementary cams 3843 and

3844, that are keyed to the shaft 330, start to drive a pair of roller followers 3847 and 3848. The rollers are pivoted on a pawl rocker 3850, which is freely mounted on the shaft 3125, and drives the rocker 3850 CW. Slots 3852 and 3853 in the locking pawl 3821 are engaged with the studs 3823 and 3825 which extend from the pawl rocker 3850. The locking pawl 3821 is carried CW thereby with the pawl rocker 3850, the ear 3829 riding rightward along the surface 3831 of the shroud 3833. The CW rocking of the rocker 3850 is indicated on line 39B (FIG. 39). At 100° of the machine cycle, the locking pawl ear 3829 is carried to a position opposite a tooth space 3855 (FIG. 38C) to the right of the shroud surface 3831. The spring 3827 pulls the ear 3829 into the tooth space 3855, engaging the locking pawl 3821 with the spacing gear 3841. As the pawl rocker 3850 is rocked further CW from 100° to 140°, the locking pawl ear 3829 drives the spacing gear 3841 CW two tooth spaces CW to a space 3857. At 140° the pawl rocker complementary cams 3843 and 3844 dwell and hold the pawl rocker 3850 and locking pawl 3821 in the CW position to which they are driven at 140°. At 140°, as indicated on line 5C (FIG. 5), the complementary cams 3127 and 3129 (FIG. 31) start to drive the platen 327 leftward into engagement with the printing segments 311 in the manner discussed hereinbefore. A platen gear 3143 (FIG. 38A), which is keyed to the platen shaft 3137, is in continuous engagement with the spacing gear 3841. The driving of the spacing gear 3841 two tooth spaces CW drives the platen gear 3143 two tooth spaces CCW thereby moving the blank line 3809-1 two spaces CCW to a position 3809-3. As the platen 327 is driven leftward from 140° to 160°, the platen gear 3143 is rotated about the spacing gear 3841 and is driven one more space CCW, bringing the blank line 3809-1 to the position 3809 prior to the platen 327 being driven against the print segments 311.

At 160° of the machine cycle the platen shaft 3137 is in a position 3137-A, indicated on line 5C (FIG. 5), in which the platen 327 is not yet in engagement with the segments 311. Referring to line 39A (FIG. 39), the locking pawl 3821 and ear 3829 are driven out of engagement with the spacing gear 3841 from 160° to 180°. Disengagement of the locking pawl 3821 from the spacing gear 3141 at this time is necessary to prevent further rotation of the platen as it is rocked against the segments 311 and of consequent smearing of the printing due to such rotation. Referring to line 5C (FIG. 5), from 180° to 200° the platen 327 is rocked towards the printing segments 311 to the position 327-A, the shaft 3137 being moved to a position 3137-B; from 200° to 220° the platen dwells in positions 327-A, against the segments 311, to permit the ink to run from the ribbon into the paper, the shaft 3137 remaining in the position 3137-B; and from 220° to 240° the platen is removed from the segments, the platen shaft moving from the position 3137-B to the position 3137-A.

In order to maintain the platen 327 in position while the locking pawl ear 3829 is out of engagement with the spacing gear 3841 during the printing period, a centralizer comprising an arm 3145 (FIG. 31) and a roller 3147 is provided. The centralizer arm 3145 is mounted on the shaft 3125 and carries the roller 3147 into engagement with a tooth space on a centralizer gear 3149 which is keyed to the platen shaft 3137. The roller 3147 is forced into engagement with the gear 3149 by a spring 3151 connected between the centralizer arm 3145 and the platen shaft 3137. From 240° to 260° line 39A, the pawl driver cam 3813 permits the locking pawl ear 3829 to drop back into engagement with the spacing gear 3841 in the same tooth space from which it was previously disengaged. Engagement occurs in the same tooth space 75 since the locking pawl 3821 is maintained in the CW

position from 140° to 260° by the rocker 3850 as indicated in line 39B.

From 260° to 320°, line 39B, the locking pawl 3821 and ear 3829 are driven CCW by the cams 3843 and 3844 three spaces from position 3857 to the CCW position of FIG. 38B. Since the locking pawl pawl ear 3829 is engaged with the spacing gear 3841 during such rocking, the right edge of the shroud 3833 is engaged by the ear 3829 and is driven one tooth space CCW against the urging of the spring 3835. The platen gear 3143 is driven CW thereby a total of three tooth spaces, feeding the new line of printing three spaces from the line of pressure position 3811 to the position 2809-1. Each tooth space of both the spacing gear and platen gear corresponds to the spacing of the lines of printing. At the same time that the gear 3841 is driven CCW, the platen shaft 3137 is returned rightward from position 3137-B to the position shown in FIG. 38A from 260° to 280°, line 5C (FIG. 5). The rightward movement of the platen gear 3143 against the spacing gear 3841 drives the platen 327 one additional space CW thereby feeding the new line of printing to the first viewing position at 3809-A, four spaces from the printing position 3809. At 320° of the machine cycle, line 39A, the locking pawl ear 3827 is driven out of engagement with the spacing gear 3841, permitting the shroud 3833 to rock CW to the position indicated in FIG. 38C.

Double space printing

Generally, listings and total, subtotal and quotient values which follow listings are single spaced from each other. Any value printed below a total, subtotal or quotient value, however, is normally double spaced two lines from such values. Double spacing between listings, total, subtotal and quotient values is accomplished by moving a double space lever 3856 (FIG. 38A) from the position indicated in the figure to a position 3856-A. Any value printed below a total, subtotal or quotient value with the double space lever 3856 in the position 3856-A is triple spaced, i.e. spaced three lines from such values.

Double spacing after printing a total, subtotal or quotient value.—Total, subtotal and quotient values are normally printed a single space beneath the preceding line of printing in the manner discussed under "Single Space Printing". In normal operation, during a total, subtotal or print quotient cycle, provision is made to condition the platen controls for double spacing the platen 327 during the next cycle which calls for printing.

The two space driver lever 3801 (FIG. 38) is pivoted on the right end of the symbol rack 3001 at 333 along with a standard rack latch 332. The rack latch 332 operates with the symbol rack in the same manner as the latches 332 on the main members 301 (FIG. 3), discussed hereinbefore.

During a total, subtotal or print quotient cycle the symbol rack 3001 is stopped against one of the steps 3005, 3011 or 3033 respectively of the plate 3003 (FIG. 30) in the manner discussed hereinbefore. With the rack 3001 stopped, the rack drive shaft 408 continues moving rightward, out of the notch 331, camming the latch 332 into engagement with the locking comb 337, thereby holding the symbol rack in the position to which it is driven. As the shaft 408 continues rightward, the upper edge of the two space driver 3801 is engaged, forcing the ear 3803 CW. If the symbol rack 3001 is stopped in a quotient, total, or subtotal position, the ear 3803 is in a position 3803-Q, 3803-T or 3803-S respectively and is driven against the nose 3805, rocking the arm 3807 and the shaft 3733 CW. An arm 3859 is keyed to the shaft 3733 and is rocked CW thereby, against the urging of a spring 3861. With the rack 3001 stopped in other positions, the two space driver ear 3803 misses the nose 3805 and is idly driven CW having no effect on the arm 3859. Clockwise rocking of the arm 3859 drives a two space link 3863, connected between the

arm 3859 and a bellcrank 3864, downward, rocking the bellcrank CW about a frame shaft 3866. A stud 3867, extending from the bellcrank, is engaged in a slot 3869 in the double space hook 3839, which hook is pivoted at 3895 on the double space lever 3856 (FIG. 38A). The lever 3856 is normally held in the position shown by a detent lever 3871. A spring 3872 forces a stud 3874 extending from the lever 3871, into engagement with a single space notch 3875 formed in the lower end of the double space lever 3856. Normally, during a total, subtotal or quotient cycle, the double space lever 3856 and hook 3839 are held in the positions indicated in FIG. 38, restraining the shroud 3833 from CW movement by engagement of the hook with the stud 3837. At 100° (line 39A, FIG. 39) of such a cycle, the locking pawl 3821 is driven into engagement with the spacing gear 3841 and from 100° to 140° (line 39B) drives the gear two spaces CW in the manner discussed hereinbefore.

Upon rocking of the bellcrank 3864 during a print quotient, total, or subtotal cycle (between 120° and 175°), the bellcrank stud 3867 rocks the hook 3839 CCW to a position which permits the stud 3837 on the shroud to move CW against a lower surface 3877 in the hook 3839, permitting the shroud 3833 to rock CW one tooth space. The bellcrank is held CCW from approximately 120° to 200° of the cycle while the symbol rack is latched rightward. A nose 3878, which extends from a two space latch 3879 and is pivoted on the double space lever 3856 at 3880, is urged CCW by a spring 3881. The spring is connected between the latch 3879 and lever 3856 and urges the latch against a stud 3883 which extends from the double space hook 3839. During a total, subtotal and quotient cycle, CW rocking of the bellcrank 3864 drives the hook 3839 and stud 3883 far enough CCW to clear the nose 3878 so that it may drop in front of the stud 3883 and latch the hook 3839 CCW. From 160° to 180°, line 39A, the pawl 3821 carries the ear 3829 out of engagement with the gear 3841. At this time, a stud 3885 that extends from the pawl 3821 is in a position 3385-A (FIG. 38), clear of the latch 3879. The ear 3829 is re-engaged with the gear 3841 from 240° to 260°, line 39B (FIG. 39), and from 260° to 320°, the ear 3829 drives the gear 3841 CCW so that the platen is fed four spaces as discussed before. The total, subtotal or quotient value is advanced thereby to the viewing position 3809-A. From 320° to 340°, line 39A, the ear 3829 is disengaged from the spacing gear 3841, freeing the shroud 3833 to rock CW under urging of the spring 3835 to a position in which the stud 3837 is blocked against the hook surface 3877 before the stud 3885 engages and drives the latch 3879 far enough to unlatch the latch from the stud 3883. When unlatched, the hook 3839 is rocked slightly CW against the stud 3837, which stud is against the surface 3877 but far enough CW to prevent the latch 3879 from re-engaging the stud 3883. With the stud 3837 in this position, the shroud 3833 is one tooth space CW from the normal position. The locking pawl ear 3829 is prevented thereby from entering the usual tooth space 3855 (FIG. 38C) during the next printing cycle.

During the next cycle which calls for printing after a total, subtotal or print quotient cycle, the locking pawl ear 3829 is moved downward from 60° to 80° (line 39A) against the shroud surface 3831. From 80° to 100° (lines 39A and 39B), the ear 3829 is driven rightward along the surface 3831, sliding downward into a tooth space 3886 (FIG. 38C) at 120°, one tooth space further rightward than normal. The ear 3829 continues to be driven from 120° to 140° of the cycle, driving the spacing gear 3841 and the platen gear 3143 one space, backspacing a blank space 3809-2 (FIG. 38A) one space CCW. As the platen 327 is driven leftward in the manner discussed hereinbefore, the platen is backspaced an additional space, moving the original blank space 3809-2 to the line of

pressure 3811. The ear 3829 is removed from engagement with the gear 3841 from 160° to 260° while printing is carried out and then re-engaged. From 260° to 320° the ear 3829 drives the gears 3841 and 3143 four spaces, feeding the tape 328 four spaces in the manner discussed. During this period the shroud 3833 is engaged by the ear 3829 and driven CCW therewith. The stud 3837 is moved thereby out of engagement with the hook surface 3877. This permits the spring 3861 to rock the hook 3839 CW to the position shown. After disengagement of the ear 3829 with the gear 3841, the shroud 3833 is rocked CW to the position shown in which the stud 3837 is blocked in the normal position by the hook 3839.

Double space lever.—In order to normally print listings and total, subtotal and quotient values which follow listings double spaced from each other, the double space lever 3856 is moved from the position in which it is shown to the position 3856-A. The lever 3856 is rocked CW thereby about the shaft 3125, forcing the detent stud 3874 to a double space notch 3888 to hold the double space lever 3856 in the position 3856-A. Since the double space hook 3839 is pivoted at 3895 on the double space lever 3856, moving the lever 3856 to the position 3856-A also carries the hook 3839 one tooth space CW from the position shown. This permits the shroud 3833 to rock CW one tooth space, bringing the shroud surface 3831 over the tooth space 3855 and blocking the ear 3829 from engagement with the gear 3841 in this space. During CW rocking of the pawl 3821 from 80° to 140° lines 39A and 39B (FIG. 39), the ear 3829 rides on the shroud until opposite the tooth space 3886 with which it becomes engaged at 120°. The ear 3829 then drives the gear 3841 one tooth space CW while the platen is toggled CCW for printing. The platen 327 is driven thereby two spaces CCW so that values or symbols may be printed on line 3809-2 as presented in the preceding discussion. The platen is then driven four spaces CW to feed the tape 328 and the new line of printing four spaces to the first viewing position, as discussed.

Triple spacing

Triple spacing occurs during a printing cycle which follows a total, subtotal or print quotient cycle if the double space lever 3856 is in the double space position 3856-A.

With the double space lever 3856 in the position 3856-A, the double space hook 3839 is rocked one tooth space CW as discussed above. During a total, subtotal or quotient printing cycle, hook 3839 is latched in the CW position by the nose 3878, with the stud 3837 against the surface 3877 by means including the lever 3801 discussed before. With the stud 3837 against the surface 3877 and the hook 3839 one tooth space CW, the shroud is rocked CW by the spring 3835 to a position in which the surface 3831 blocks the ear 3829 from engaging the spacing gear 3841 in tooth spaces 3855 and 3886. The locking pawl 3821 is lowered against the surface 3831 from 60° to 80° as indicated on line 39A (FIG. 39). The pawl 3821 is then rocked CW from 80° to 140°, carrying the ear 3829 rightward along the surface 3831. At 140° of the cycle, as indicated on lines 39A and 39B, the ear 3829 drops into the tooth space 3857. Since CW rocking of rocker 3850 and pawl 3821 is completed at 140°, the spacing gear 3841 is not rocked by the pawl ear 3829; however, the ear 3829 holds the spacing gear 3841 in position while the platen 327 is rocked leftward in the manner discussed hereinbefore. During this period the platen gear 3143 is rocked one tooth space CCW. A blank space 3809-3, spaced three lines from the preceding line of printing at 3809-A, is moved thereby to the line of pressure 3811 for printing. After printing, from 180° to 240° line 5C (FIG. 5), in the manner discussed previously, the platen 327 is driven four spaces CW feeding the tape four spaces

and bringing the new line of printing to the first viewing position at 3809-A.

No printing and no paper advance

5 It is recalled that during a cycle which calls for printing, the enabling lever 3111 (FIG. 31) is rocked CCW, in a manner discussed elsewhere, to enable the mechanism in FIG. 31 to rock the platen 327 leftward for printing. The enabling lever 3111 is keyed to the shaft 3107, rocking the shaft CCW. An enabling hook 3890 (FIG. 38B) is also keyed to the shaft 3107 and is rocked CCW thereby with the shaft, out of the path of a stud 3891 which extends from the pawl driver 3817. The driver 3817 is free therefore to follow the cam 3813 during a printing cycle.

15 During other cycles which do not call for printing, the hook 3890 remains in the position shown, blocking the pawl driver 3817 from moving downward during rotation of the cam 3813. Such blocking, maintains the locking pawl each 3829 out of engagement with the spacing gear 3841. The locking pawl 3821 therefore idly rocks CW and CCW without either backspacing or advancing the platen 327. Neither is the platen driven leftward by the lever 3123 since the enabling lever 3111 is maintained in the CW position shown in FIG. 31, keeping the stud 3113 clear of the notch 3117. Therefore, no back spacing, printing, or paper advance is carried out during such cycles.

CONTROL KEY CONDITIONING MECHANISM

30 A control key conditioning mechanism 4000 (FIG. 40) is provided as part of the controls necessary to enable the add total key 103 (FIG. 1), the subtotal-correction key 105, the nonadd key 109, the multiplier entry key 110 and the subtotal = key 114 to function as multifunction control keys, and further, to enable the divide key 118 for effective operation and to interlock the dividend tab key 120. The operation which is carried out upon depression of one of these keys depends on whether the pin carriage 205 (FIG. 23) is or is not in the normal "home" order. The normal home order corresponds to the rack assembly 300-4, and the pin carriage is said to be in the normal home order whenever the highest order pin carriage pins 304-Z are lined up with the fourth order rack assembly 300-4. This is the position of the pin carriage prior to entry of any value therein. With the pin carriage in this home order, depression of any one of the multifunction keys 103, 105, 109 and 114 initiates a first operation. With the pin carriage 205 escaped one or more orders 45 leftward from the normal home order as a result of a value entry, depression of a function key initiates a different operation.

50 The divide key 118 is not a multifunction key but is enabled for operation by means including the mechanism 4000. With the pin carriage in the normal home order, depression of the divide key is ineffective and does not initiate any operation. This prevents division by zero. With the pin carriage escaped leftward, a division operation 55 is initiated upon depression of the divide key.

The dividend tab key 120, also is not a multifunction key, but is under control of the control key conditioning mechanism 4000. The key 120 is blocked from depression when no value is represented in the pin carriage, and is not blocked upon escapement of the pin carriage leftward from the home position after a value entry therein. This arrangement also prevents escapement leftward of the pin carriage and division by zero.

65 70 Neither can a value be entered into the pin carriage by means of the 0 value key for enabling the divide key. Initial escapement leftward of the pin carriage by depression of the 0 value key is prevented by a fixed pin in the 0 position of the leftmost order of pins 304-Z (FIG. 75 23).

Add-total key

Depression of the add-total key 103 (FIG. 1) with the pin carriage 205 in the home order initiates a total cycle; however, after escapement of the pin carriage one or more orders leftward from the home order and actuation of the control key conditioning mechanism 4000, depression of the key 103 initiates an add cycle.

Total cycle.—As presented previously in the "Add-Total Key, Total Debit Function" discussion, the total power link 2805 (FIG. 28) is power driven rightward during every machine cycle. The link 2805 is maintained in the raised position shown if the pin carriage is in the home order and is lowered to the position 2807-A when the pin carriage is escaped leftward by means presently described. During a total cycle, however, the pin carriage 205 is in the home order, leaving the link 2805 in the raised position. As the link 2805 is driven rightward, the shoulder 2807 engages the total control pinning stud 2809 (FIGS. 28 and 29), driving the stud rightward and the link 2907 (FIGS. 18 and 29) leftward. Leftward movement of the link 2907 forces the shaft 1813 to a position in which the rounded forward blocking surfaces 1811-A and 1811-B of the carry blocking elements 1811, which are mounted on the shaft 1813, block the carry teeth 1821 from CW rotation from the 0 position shown or CCW rotation from the nine position 1821-A. Such blocking stops the racks 303 from further rightward movement during a total cycle after a value in the accumulator register 207 is transferred to the racks 303. The printing segments 311, being connected to the racks 303, are rotated to the same value position of the racks in order that the value may be printed.

Add cycle.—Whenever the pin carriage 205 is escaped one or more orders leftward, the total power link 2805 is lowered out of the path of engagement with the control stud 2809. The carry-blocking elements 1811, therefore, are not driven leftward to block the numeral wheels and racks as during a total cycle, but leave the wheels free to receive the entire value from the racks. In order to lower the link 2805 away from the stud 2809, a tail 2313 (FIGS. 23 and 40) is suitably mounted on the pin carriage 205 and extends rightward therefrom into engagement with a roller 2315 mounted on an arm 4001 (FIG. 40). The arm 4001 is keyed to a shaft 4003 which is urged CCW by an arm 4101 (FIG. 41). The arm 4101 is also keyed to the shaft 4003 and is urged CCW by a spring 4103. Entry of a value into the pin carriage 205 escapes the carriage leftward, carrying the tail 2313 out of engagement with the roller 2315. The arms 4101, 4001 and shaft 4003 are rocked CCW under the urging of the spring 4103. As the arm 4001 is rocked CCW, an ear 4005, which extends therefrom, drives a live tip 4007, loosely mounted on the shaft 4003, CCW. The live tip 4007 normally restrains a stud 4009, extending from a lever 4011, from movement CW about a frame shaft 4013 under the urging of a spring 4015. As the live tip 4007 is driven CCW, the stud 4009 and lever 4011 are released for CW movement. A nose 4017, formed on the upper part of the lever 4011 is driven thereby against an ear 4019 on a latch control bellcrank 4021 (FIGS. 28 and 40), forcing the bellcrank CCW about a frame shaft 4023 against the urging of a spring 4025. A total control link 2831, having a stud 2833 on the left end of the link in engagement with a slot 2835 in the bellcrank 4021, is forced leftward as the bellcrank is forced CCW. The right end of the link 2831 is fastened to the total control lever 2811, driving the lever CCW about a frame shaft 2837. As the total control lever 2811 is rocked CCW, the stud 2813 in the slot 2815 in the total power link 2805 rocks the link CCW, lowering the shoulder 2807 to the position 2807-A clear of the total control stud 2809. Thus, during a machine cycle which is initiated by depression of the add-total key 103 with a

value in the pin carriage, the total power link 2805 is driven rightward with the shoulder 2807 clearing the stud 2809. The carry-blocking element 1811 (FIG. 18) is maintained thereby in the position shown so as not to block the rightward movement of the racks 303 (FIG. 3).

5 A bifurcated right arm of the bellcrank 4021 is engaged with the ear on the control slide latch 915 (FIGS. 9, 28 and 40). Counterclockwise rocking of the bellcrank 4021 in addition to lowering the link 2805, rocks the control slide latch 915 from the position shown to the position 915-A. As discussed hereinbefore in the "Adding Machine Keys and Mechanism" section, with no value in the pin carriage, the latch 915 is in the position shown and depression of the add-total key 103 initiates a total cycle; otherwise, with a value in the pin carriage the latch 915 is in position 915-A and depression of the add-total key 103 initiates an add cycle during which the value in the pin carriage is transferred to the accumulator register 207.

10 Near the end of an add cycle, during the period that the pin carriage is cleared, the control key conditioning mechanism 4000 is restored to the positions shown in FIG. 40. As discussed hereinbefore under "Pin Carriage Clearance," a shiftable clear plate drive link 2548 (FIG. 25) is driven rightward during pin carriage clearance. A restore link 2560 (FIGS. 25 and 40) is connected to the left end of the drive link 2548 at 2549 and is carried rightward by the link 2548 during pin carriage clearance. A slot 4027 in the left end of the restore link 2560 (FIG. 40) is engaged with a stud 4029 extending from the lever 4011. When the link 2560 is driven fully rightward, the lever 4011 is driven CCW against the spring 4015. The nose 4017 is moved thereby away from the ear 4019, permitting the spring 4025 to rock the bellcrank 4021 CW and the latch 915 CCW to the position shown.

15 During a pin carriage clearance the pin carriage is driven rightward in the manner discussed hereinbefore, carrying the tail 2313 into engagement with the roller 2315, forcing the arm 4001 CW to the position shown. The live tip 4007 is resiliently held to the arm 4001 by a spring 4013 and is carried thereby to the position shown, blocking the stud 4009 and lever 4011 from rocking CW after the link 2560 is returned rightward.

Subtotal-correction key

20 With no value in the pin carriage, depression of the subtotal-correction key 105 initiates a subtotal cycle, and with a value in the pin carriage the control key conditioning mechanism 4000 is actuated so that depression of this key initiates a correction cycle.

25 *Subtotal cycle.*—Depression of the subtotal-correction key 105 with no value in the pin carriage, initiates a subtotal cycle during which the control slide blocking element 1301 (FIG. 13) is moved to the position 1301-D. Since there is no value in the pin carriage, the control slide latch 915 (FIG. 9) is maintained in the CCW position shown. The control slides 901 are thereby controlled, in the manner discussed hereinbefore under "Subtotal-Correction Key, Correction Function," to bring the accumulator register 207 into the racks 303 at the proper time and in the proper direction to carry out a subtotal cycle. Since there is no value in the pin carriage during a subtotal cycle, the total power link 2805 engages the stud 2809 and forces the carry-blocking element 1811 (FIG. 18) into the position for blocking the tens carry teeth 1821 in the manner discussed.

30 *Correction cycle.*—With a value in the pin carriage, the control slide latch 915 is maintained in the position 915-A as discussed above so that when the total power link 2805 is driven rightward, it is clear of the total control stud 2809. Depression of the subtotal-correction key 105 under these conditions initiates a correction cycle. Although the control slide blocking element 1301 is moved to the posi-

tion 1301-D, the same position as during a subtotal cycle, the control slide latch 915 is in the position 915-A so that the control slides 901 are controlled to maintain the accumulator register 207 out of engagement with the racks 303 in the manner discussed hereinbefore under "Subtotal-Correction Key, Correction Function." The significant operation carried out as a result of the depression of the subtotal-correction key 105, under these conditions, is clearing of a pin carriage as discussed under "Pin Carriage clearance."

Multiplier entry key

Depression of the multiplier entry key 110 (FIG. 1) releases the multiplier plate 2714 (FIG. 27) to one of three possible active positions to carry out one of three corresponding multiplier entry cycles. Such depression also causes the motor to start and leaves the key 110 latched in the depressed position.

Depression of the multiplier entry key 110 drives the depending lever 3515 (FIG. 36) CCW about a frame shaft 629 (FIGS. 35 and 36) against the urging of a spring 3527. A stud 3529 extends from the multiplier entry key lever 3515 into engagement with a slot in a keystem 3531 so that when the lever 3515 is forced downward by depression of the key 110, the stem 3531 also is driven downward. A slot in the lower end of the stem 3531, which is engaged with a stud 4201 (FIG. 42) that extends from a latching lever 4209a, drives the lever CCW about a frame shaft 4207. An ear 4209 formed on the right end of the latch 4209a rises, permitting a hook position 4211 of a latch 4213 to rock CCW beneath the ear 4209 under the urging of a spring 4215. The lever 4209a the key stem 3531 and the multiplier entry key 110 are latched thereby in the depressed position.

Normally, an ear 4217 that extends from the key stem 3531 (FIGS. 27 and 42) is engaged with a shoulder 2724 in the multiplier plate 2714, thereby restraining the plate 2714 from movement leftward under the urging of a spring 2726. Lowering of the key stem 3531 carries the ear 4217 to the position 4217-A clear of the shoulder 2724, releasing the multiplier plate 2714 for movement leftward by the spring 2726. Such movement starts the motor and engages the main clutch 801 (FIG. 8) in a manner discussed hereinafter in the "Program Unit" section. The plate 2714 including the shoulder 2724, during such movement, may be stopped in any one of three positions: 2714-X_{KB}, 2714-X_A, or 2714-X_C.

In a manner fully discussed hereinafter, but only generally here, the plate 2714 is stopped in the position 2714-X_{KB} if the pin carriage is escape leftward as a result of a value entry prior to depression of the multiplier entry key 110, in which case the value in the pin carriage 205 (FIG. 2) is transferred to the multiplier and counter registers 209 and 211 (a keyboard multiplier entry cycle). The multiplier plate 2714 is stopped in the position 2714-X_A if the subtotal equals key 114 is depressed prior to depression of the multiplier entry key 110, in which case an accumulator register multiplier entry cycle is carried out during which a value in the accumulator register 207 (FIG. 2) is transferred to the multiplier and counter registers 209 and 211 over leads 219 and 221. If the multiplier plate 2714 is stopped in the position 2714-X_C, the pin carriage is in the home order and the subtotal = key 114 is not depressed prior to depression of the multiplier entry key 110, in which case a counter register multiplier entry cycle is carried out during which a value in the counter register 211 is transferred to the multiplier register 209 over the lead 223.

Upon depression of the multiplier entry key 110 and release of the multiplier plate 2714, mechanism including the control key conditioning mechanism 4000 (FIG. 40) is effective to block the plate 2714 in the position 2714-X_{KB} if there is a value in the pin carriage, and if

not, permits the plate 2714 to move further leftward to either the position 2714-X_A or 2714-X_C. A back latch 4219 (FIG. 42) is provided with an ear 4221 which is carried to a position 4221-A to the left of a shoulder 2728 in the multiplier plate 2714 whenever a value is entered into the pin carriage. The ear 4221 is carried to the position 4221-A by the following means. Entry of a value into the pin carriage escapes the pin carriage leftward carrying the tail 2313 out of engagement with the roller 2315 (FIGS. 23 and 40), permitting the arm 4001, the arm 4101 (FIG. 41) and the shaft 4003 to rock CCW under the urging of the spring 4103, in the manner discussed hereinbefore. A stud 4114, extending from the arm 4101, drives a live tip 4116 CCW out of blocking engagement with a shoulder 4117 on a pin carriage home order slide 4119, releasing the slide 4119 for movement leftward under the urging of a spring 4121. A stud 4123 on the slide 4119 is carried leftward into engagement with a nose 4124 of a backlatch lever 4126, driving the lever CCW about a frame shaft 4127. A stud 4120 extending from the lever 4126 engages a projection from the backlatch thereby driving the backlatch upward against the urging of a spring 4223, carrying the ear 4221 (FIG. 27) to the position 4221-A to block the multiplier plate 2714 in the position 2714-X_{KB} (FIG. 27) upon depression of the multiplier entry key 110.

It is thus seen that the control key conditioning mechanism and the latch 4219 either blocks the multiplier plate 2714 in the position 2714-X_{KB} or permits the plate to move past this position to either the position 2714-X_A or X_C, and that the entry or lack of entry of a value into the pin carriage is one of the preconditions which enables the multiplier entry key 110 to be used as a multifunction key, other preconditions being discussed hereinafter.

Subtotal = key

As discussed in the General Description, the subtotal = key 114 (FIG. 1) may be used in two ways: first, to set up a X_A multiplier entry cycle; and second, to initiate a multiplication operation. To set up a X_A multiplier entry cycle, during which cycle the value in the accumulator register 207 (FIG. 2) is transferred to the multiplier and counter registers 209 and 211, the subtotal = key 114 is latched down either from a previous subtotal multiplication operation, or by depression prior to depression of the subtotal = key. Second, the subtotal = key 110 may be used to initiate a multiplication operation during which the product is subtotalled. In both the first and second cases, the subtotal = key is latched in and released from the depressed position by a subtotal = key latch 4133 (FIG. 41) under control of the Control Key Conditioning Mechanism 4000 (FIG. 40).

Multiplier entry cycle using subtotal = key.—Use of subtotal = key 114 in initiation of a multiplier entry cycle during which the value in the accumulator register 207 is transferred to the multiplier and counter registers 209 and 211, results in the subtotal = key 114 and the multiplier entry key 110 being latched in the depressed position throughout the multiplier entry cycle, the multiplier entry key remaining latched at the end of the cycle while the subtotal = key is released near the end of the cycle.

Depression of the subtotal = key 114 drives a depending lever 3533 (FIGS. 35 and 36) CCW about the frame shaft 629 against the urging of a spring 3535. A stud 3537 extends from a subtotal = key stem 3539 into engagement with a slot in the lever 3533 so that as the lever 3533 is forced downward, the stem 3539 is also driven downward. A nose 4135, extending from the subtotal = key latch 4133 (FIG. 41), is normally against an ear 4137 extending from the keystem 3539. A spring 4139 is connected between the frame and a subtotal = key latch lever 4141 which is pivoted on the latch 4133. The spring 4139 urges the latch 4133 and lever 4141 leftward, forc-

ing the nose 4135 against the ear 4137. Depression of the subtotal = key 114 drives the stem 3599 downward to a position in which the nose 4135 rocks over the ear 4137, latching the key 114 and stem 3539 in the depressed position.

With the subtotal = key keystem 3539 lowered, an ear 4143, extending from the stem 3539, is carried to a position opposite a shoulder 2730 (FIG. 27) on the multiplier plate 2714. Upon depression of the multiplier entry key 110, the multiplier plate 2714 is released to move leftward until blocked by the ear 4143 in the position 2714-X_A. The ear 4221 is clear of the shoulder 2728 since the value keys 101 are not depressed at this time. The multiplier entry key 110 and subtotal = key 114 are therefore used together to initiate a X_A multiplier entry cycle during which a value is transferred from the accumulator register to the multiplier and counter register.

Initiation of a multiplication operation using the subtotal = key.—Under normal conditions, depression of the subtotal = key 114 latches the key in the depressed position. Entry of value in the pin carriage, however, disengages the nose 4135 (FIG. 41) with the ear 4137 by means presently described, releasing the keystem 3539 and key 114 to rise under the urging of the spring 3535 (FIG. 36). Further depression of the key 114 with a value in the pin carriage is idle and the key rises after the depression since the ear 4137 cannot engage the nose 4135. Furthermore, depression of the key 114 does not initiate a multiplication operation unless the machine is preconditioned by a multiplier entry cycle as discussed below.

The subtotal = key 114 must be latched down to carry out a X_A multiplier entry cycle; it is released upon entry of a multiplicand value and then again depressed and latched down to initiate a subtotal multiplication operation.

Means including the control key conditioning mechanism 4000 (FIG. 40) are provided to release the subtotal = key 114 following an X_A multiplier entry cycle to permit the key 114 to be depressed and latched following entry of a multiplicand. In order that the subtotal = key may operate as outlined above, the subtotal = key is preconditioned when the multiplier entry key 110 is depressed for initiation of a multiplier entry cycle. During entry of a multiplier value into the pin carriage prior to the multiplier entry cycle, the pin carriage is escaped leftward, carrying the tail 2313 out of engagement with the roller 2315 (FIGS. 23 and 40), permitting the arm 4001, the arm 4101 (FIG. 41) and the shaft 4003 to rock CCW under urging of the spring 4103, in the manner discussed hereinbefore. The stud 4114 extending from the arm 4101 is driven thereby against the live tip 4116, driving the live tip CCW out of blocking engagement with the shoulder 4117 on the pin carriage home order slide 4119, releasing the slide 4119 for movement leftward under the urging of the spring 4121. The stud 4123 on the slide 4119 is carried leftward into engagement with the nose 4124 of the back latch lever 4126, driving the lever CCW about the frame shaft 4127. A stud 4145 on a lower arm of the back latch lever 4126 is driven thereby against a hooked end 4147 on the subtotal = key latch lever 4141, forcing the lever rightward. The lever 4141, being pivoted on the subtotal = key latch 4133, carries the latch nose 4135 rightward out of engagement with the ear 4137 on the subtotal = keystem 3539, releasing the stem 3539 and the subtotal = key 114 to rise to the positions shown.

Release of the subtotal = key 114 to the raised position after a multiplier entry cycle, gives the operator the choice of depressing the total = key 112, the subtotal = key 114 or the negative = key 116 to initiate respective multiplication operations.

Prior to initiation of a multiplication operation by depression of the subtotal = key 114, a multiplier entry

cycle is carried out in response to depression of the multiplier entry key 110. The key 110 remains latched in the depressed position after the multiplier entry cycle is carried out by means discussed hereinafter and is not released until the completion of a multiplication operation. An ear 4149 (FIG. 41) on the keystem 3531 is therefore in a position 4149-A throughout each multiplier entry cycle and the associated multiplication operation. A multiplicand value is entered into the pin carriage after the multiplier entry cycle is carried out, prior to initiation of a multiplication operation. The ear 4149 on the multiplier entry keystem 3531 will therefore be in the position 4149-A in the path of a camming surface 4151 on the lever 4141, prior to entry of the multiplicand value into the pin carriage. Upon entry of a multiplicand value into the pin carriage, the shaft 4003 is driven CCW in the manner discussed hereinbefore and the back latch lever 4126 driven CCW, carrying the stud 4145 to a position 4145-A. The hooked end 4147 is engaged by the stud 4145 so that the lever 4141 and latch 4133 are carried rightward thereby. When the camming surface 4151 engages the ear 4149, the lever 4141 is rocked CCW thereby out of engagement with the stud 4145 so that the hooked end 4147 rides on top of the stud 4145. The latch 4133 is returned leftward carrying the end 4147 to the position 4147-A, still out of engagement with the stud 4145.

After the above conditioning, depression of the subtotal = key 114 to initiate a multiplication operation results in the ear 4137 being latched by the nose 4135, thereby maintaining the key 114 in the downward position even though a value is in the pin carriage. The subtotal = key 114 remains latched downward throughout and at the end of the multiplication operation.

During the last cycle of the multiplication operation, the pin carriage is cleared, the shaft 4003 is rocked CW thereby to the position shown, carrying the stud 4114 out of engagement with the live tip 4116. The master plate 3401 (FIGS. 41 and 44), more fully discussed hereinafter in the "Program Unit" section, is driven fully rightward during the last cycle of any operation as well as the multiplication operation, forcing a shoulder 4153 against an arm 4155 projecting from the slide 4119. The slide 4119 is driven rightward thereby, permitting the live tip 4116 to latch with the shoulder 4117 and the spring 4223 to restore the latch 4219 and lever 4126 to the positions shown. The stud 4145 is carried thereby to the left of the hook end 4147, permitting the lever 4141 to drop.

Upon depression of any value key 101, after a subtotal multiplication operation, the subtotal = key 114 and keystem 3539 are released from the downward position in the manner discussed before. If, however, it is desired to transfer the value from the accumulator register 207 to the multiplier and counter registers 209 and 211, it is only necessary to depress the multiplier entry key 110, the subtotal = key 114 already being latched downward.

ST = key release.—Whenever the ST = key 114 (FIG. 1) is inadvertently depressed or remains depressed as the result of a multiplication operation, it may be released either by entry of a value into the pin carriage in the manner discussed or by depression of the T = key 112, the N = key 116, the divide key 118, or during a cycle initiated by any of the other control keys 103, 104, 105, 107 or 109. As discussed before, depression of the ST = key 114 causes an ear 4137 (FIGS. 41 and 42A) on the keystem 3531 to move downward to a position in which the latch 4133 is rocked CCW over the ear 4137 to hold the ST = key and keystem in the depressed position. Studs 4185, 4186 and 4187 extend respectively from the divide keystem 4225, the T = keystem 4714 and the N =

keystem 4813 for unlatching the ST= keystem 3531 whenever any one of the corresponding keys 118, 112 or 116 are depressed.

For example, depression of the T= key 112 forces the stud 4185 against a camming surface 4188 of a connecting link 4189. The link is connected between a back arm 4190 and a front arm 4191, both of which arms are pivoted on frame studs. The connecting link 4189 is forced rightward thereby, rocking the front and back arms CW. A latch driver 4192 is pivoted on the upper end of the front arm 4191 at 4199 and is spring urged CCW and leftward by a spring 4193. Clockwise rocking of the front arm 4191 upon depression of the T= key drives the latch driver 4192 rightward against stud 4142. The stud extends from the latch 4133 so that the latch is driven rightward therewith, out of engagement with the ear 4137 to permit the ST= keystem 3539 and ST= key 114 to rise.

Likewise, depression of the divide key 118 drives the keystem 4225 and the stud 4185 against the front arm 4191, driving the latch driver 4192 and latch 4133 rightward to release keystem 3539 and ST= key 114 to rise. Similarly, depression of the N= key 116 drives the stud 4187 against the back arm 4190 to unlatch the ST= keystem 3539 and ST= key 114 to rise.

Depression of any other control key initiates a single cycle operation during which the master plate 3401 (FIGS. 41 and 44) is driven rightward by means discussed hereinafter, bringing a step 4430 in the plate against an ear 4194 extending from the front arm 4191. The latch driver 4192 is driven rightward thereby against the stud 4142, releasing the ST= keystem 3539 and ST= key 114 to rise.

Divide key

Depression of the divide key 118 is rendered effective only after a pin carriage entry by mechanism including the control key conditioning mechanism 4000 (FIG. 40); otherwise, depression of the divide key is idle and ineffective.

After a value entry into the pin carriage, the backlatch 4219 (FIG. 41) is driven upward in the manner described in the preceding section. An ear 4157 on the latch 4219 normally holds a division program plate 4301 (FIGS. 41, 42 and 43) from leftward movement by engagement of the ear 4157 with a shoulder 4203 on the division plate. With the backlatch 4219 driven upward, the ear is in a position 4157-A (FIG. 41) clear of the shoulder 4203. This frees the division plate to move leftward under the urging of a spring 4305 to a position in which a shoulder 4307 is blocked by an ear 4309 (FIG. 43) on a divide keystem 4225 (FIGS. 42 and 43). Upon depression of the divide key 118 (FIGS. 1 and 35), the depending lever 3513 is lowered, driving the keystem 4225 (FIG. 42) downward. The divide key 118 and the keystem 4225 are connected together in an arrangement (not shown) similar to that between the multiplier entry key 110 and the keystem 3531 (FIG. 36). The ear 4309 is carried out of engagement with the shoulder 4307, releasing the division plate for movement fully leftward to an active position to initiate and carry out a division operation in a manner fully discussed hereinafter in the "Program Unit" section. In moving to an active position, the division plate 4301 passes over the ear 4309, latching the divide key 118 and keystem 4225 downward. During the last cycle of a division operation, the plate 4301 is relatched with the ear 4157 in a manner discussed hereinafter, permitting the keystem 4225 and divide key to rise to normal position.

Thus, prior to partial release of the division plate as a result of a keyboard entry, depression of the divide key has no effect since the plate is held by the ear 4157.

Interlocking with respect to the multiplier entry key 110 is provided when the division plate 4301 is leftward in an active position. A shoulder 4311 on the plate is in a position 4311-A (FIGS. 42 and 43) beneath an ear 4227, thereby blocking depression of the multiplier entry key 110 after a division operation is initiated. Interlocking is provided with respect to other keys by means discussed hereinbefore in the "Keyboard Interlocking" section.

Nonadd key

As with the other dual function keys the nonadd key 109 (FIG. 6) is preconditioned by the control key conditioning mechanism 4000 (FIG. 40) which, in this case, responds to the pin carriage being either in or not in the home order to control the machine to either print a stored multiplier value or to print the value in the pin carriage and then clear the pin carriage.

Depression of the nonadd key 109 with no value in the pin carriage initiates a multiplier readout cycle during which the counter register 211 (FIG. 2) is lowered into engagement with the rack teeth 352 (FIG. 3) so that a multiplier value stored in the counter register is printed and then restored to the register. Depression of the nonadd key after a pin carriage entry initiates a nonadd cycle during which the value in the pin carriage is printed and the pin carriage is cleared.

Multiplier readout cycle.—Depression of the nonadd key 109 (FIG. 6) rocks the depending right arm of the nonadd bail 640 downward about the shaft 629. The stud 642 extending from the left arm of the bail 640 is rocked downward against the nonadd trip slide 644 to disengage the trip slide from an ear 646 extending from a frame bracket to permit the spring 648 to move the trip slide forward. Forward movement of the trip slide starts the motor and initiates the cycle in the manner discussed hereinbefore in the "Adding Machine Keys and Mechanism" section. A nonadd lever 650 (FIGS. 6 and 41), having an upward extending stud 4159 in engagement with a bent rearward end 4161 of the trip slide 644 and a bracket 4163 fastened thereto, is rocked CW about a frame shaft 652 as the trip slide 644 is moved forward. A tail 654 on the nonadd lever is in engagement with a bifurcated end of a lever 4165, rocking the lever CW about a frame shaft upon forward movement of the trip slide 644. A stud 4167, on the right end of the lever 4165, is in engagement with a bifurcated end of a nonadd interponent 4169. The interponent 4169 is pivoted at 4171 on the slide 4119 and is rocked CCW by the stud 4167, driving a tail 4173 against a stud 4175 on a nonadd bellcrank 4177, rocking the bellcrank CCW about a frame shaft 4179. An ear 4181 is rocked upwards by the bellcrank to a position 4181-A. The ear 4181 is part of the multiplier and counter register controls 231 (FIG. 2) which includes a register drive mechanism, all of which are fully discussed hereinafter.

Generally, the register drive mechanism raises, lowers and neutralizes the multiplier and counter registers 209 and 211, and during a multiplier readout cycle is preconditioned to lower only the counter register 211 into engagement with the rack teeth 352 by movement of the ear 4181 to the position 4181-A. The counter register 211 is maintained in engagement with the racks 303 during both the right and left stroke of the racks, blocking the racks in the multiplier value position during the rightward stroke and receiving the value from the racks during the left stroke. The printing segments are driven thereby to the multiplier value positions and the multiplier value is printed in the manner discussed hereinbefore.

Nonadd cycle.—Upon entry of a value into the pin carriage, the pin carriage home order slide 4119 releases the carriage for movement leftward in the manner discussed hereinbefore. The nonadd interponent 4169, which

is pivoted at 4171 to the pin carriage home order slide 4119, is carried leftward with the slide to a position in which the tail 4173 is clear of the stud 4175. Upon depression of the nonadd key 109, the nonadd interponent 4169 is rocked CCW in the manner discussed above; however, since the nonadd interponent is leftward, the tail 4173 misses the stud 4175 on the nonadd bellcrank 4177, leaving the bellcrank and ear 4181 in the position shown. With the ear 4181 in the position shown, the multiplier and counter register controls 231 (FIG. 2) are not preconditioned so that the counter register 211 (FIG. 3) remains in the neutral position shown, out of engagement with the teeth 352. Thus, during a nonadd cycle the racks are driven rightward clear of all registers stopped against depressed pins 304, rotating corresponding segments 311 to value positions to print the value in the pin carriage. The pin carriage is cleared thereafter in the manner hereinbefore discussed.

Dividend tab key

The control key conditioning mechanism 4000 (FIG. 40) is responsive to the pin carriage to block the dividend tab key 120 (FIG. 19A) when the pin carriage is in the home order and to enable depression of the key after the pin carriage is escaped leftward. The dividend tab key 120 normally is depressed to escape the pin carriage 205 to the partial tab position or full tab position in the manner discussed hereinbefore under "Dividend Tab Key and Tab Stop Lever." If there is no value in the pin carriage, the dividend tab key 120 is blocked from depression by the following means.

With the pin carriage in the home order, depression of the dividend tab key 120 rocks a nose 1935, on the dividend tab key lever 1902 (FIG. 19A), against a dividend tab key interlock lever 1937 (FIGS. 19A and 35) which clocks further downward movement of the lever. Entry of a value into the pin carriage, however, rocks the arm 4101 (FIG. 41) CCW in the manner discussed hereinbefore. A tail 4183 on the upper end of the arm is engaged with the bifurcated end of the interlock lever 1937 (FIG. 35) and is rocked CCW thereby upon entry of a value into the pin carriage. The lever 1937 is driven CCW to a position 1937-A clear of the nose 1935, permitting depression of the dividend tab key 120 after a value is entered into the pin carriage.

PROGRAM UNIT

Generally, the program unit 229 (FIG. 2) is under control of the control keys 203 and is provided to control the machine 100 (FIG. 1) to automatically carry out predetermined sequences of operations during multiplication and division upon selective depression of a control key 203. The basic elements of the program unit 229 (FIGS. 2 and 42) are five function plates, two control plates and associated mechanism for control of the plates.

The function plates include the multiplier plate 2714 (FIG. 27), a correction plate 4229 (FIG. 46), a total plate 4231 (FIG. 47), a negative plate 4233 (FIG. 48), and the division plate 4301 (FIGS. 42 and 43). Each of the plates is latched in a normal position against leftward urging of respective springs. Upon depression of a control key 203, one of the function plates is released to move leftward to an active position and thereafter may be moved by associated mechanism to other active positions. Only one of the function plates is in an active position at a time.

The control plates include the master plate 3401 (FIG. 44) and a sensing control plate 4235 (FIG. 45), both of which plates are active during multiplication and division operations. Generally, release and movement leftward to an active position of a function plate as a result of a control key depression releases the master plate leftward to start the motor and unlatch the sensing plate.

During each cycle of such operations, the sensing plate senses the position of the active function plate so that other portions of the machine 100 may be controlled according to that position.

Master plate

The master plate 3401 (FIGS. 42 and 44), in addition to the functions discussed hereinbefore in the "Control Key Conditioning Mechanism" section and the "Keyboard Interlocking" section, is provided to release the sensing control plate 4235 (FIGS. 42 and 45) for movement leftward to a sensing control position and to start the motor upon release of any one of the function plates to an active position.

Extending from each of the function plates 2714, 4229, 4231, 4233 and 4301 are respective projections 2732 (FIG. 27), 4601 (FIG. 46), 4701 (FIG. 47), 4801 (FIG. 48) and 4313 (FIG. 43). Movement leftward of any one of the function plates forces the associated projection e.g. the projection 2732 (FIGS. 27 and 44) on the multiplier plate 2714, beneath a shaft 4401, thereby raising the shaft. The shaft 4401 extends through apertures 2734, 4603, 4703, and 4315 in the plates 2714, 4229, 4231, 4233 and 4301 respectively and is mounted between two levers 4403, one on each side of the plates, only one being shown. The levers 4403 are loosely mounted on a frame shaft 4405 which also extends through the apertures. The shaft 4401 is held normally in the position shown against the lower edges of the apertures by means of a lever 4407 which is also loosely mounted on the shaft 4405. The lever 4407 is urged by spring 4409 against the shaft 4401.

Depression of a control key 203 releases the corresponding function plate leftward. For example, depression of the multiplier entry key 110 lowers the keystem 3531 (FIGS. 36 and 42) to release the multiplier plate 2714 for movement leftward as discussed in the "Control Key Conditioning Mechanism" section. The projection 2732 (FIGS. 27 and 44) is forced thereby beneath the shaft 4401, rocking the levers 4403 and 4407 CCW against the spring 4409. Normally, an ear 4411 on the lever 4407 is engaged with a shoulder 4412, blocking the master plate 3401 from movement leftward under the urging of a spring 4413. Movement of the projection 2732 beneath the shaft 4401 forces the shaft against the lever 4407, raising the lever and ear 4411 and releasing the plate 3401 to move leftward until the shoulder 4412 is stopped against the shaft 4401. During such movement, a shoulder 4415 engages an ear of a motor starting lever 4417 (FIGS. 12 and 44) and rocks it CW about a frame shaft 4419. Clockwise rotation of the lever 4417 rocks the back starting lever 1210 CW (FIG. 12), unlatching the back starting link 1216 for movement leftward to start the motor and engage the main clutch 801 (FIG. 8) in the manner discussed in the "Motor Starting and Main Clutch Engagement" section hereinbefore.

Also, during leftward movement of the master plate 3401, a notch 4421 engages an ear 4423 (FIGS. 44 and 45) on an interponent 4501. The interponent is formed with a slot 4503 which is engaged with a stud 4504 on a latch lever 4505. The lever 4505 is loosely mounted on the shaft 4405. The interponent is spring urged CW and rightward by a spring 4507 and is prevented from further CW rotation by engagement of an edge 4509 with the shaft 4401. The latch lever 4505 is normally maintained thereby in blocking engagement with a stud 4511 on the sensing control plate 4235, preventing the plate from being spring urged leftward by means presently described. Leftward movement of the master plate brings the notch 4421 into engagement with the ear 4423 and drives the interponent 4501 leftward driving the right edge of the slot 4503 against the stud 4504. The latch lever 4505 is rocked CCW thereby, out of engagement with the stud 4511, releasing

the sensing control plate 4235 for movement leftward to the sensing control position. In this position the right edge of a slot 4513 is against a supporting shaft 4514 which extends through similar slots in the other program plates.

Sensing control plate

Sensing elements are cyclically released by means of the sensing control plate 4235 (FIG. 45) to sense surfaces of an active function plate during multiplication and division operations. The sensing elements include an accumulator sensing slide 4515 (FIGS. 27, 43, 45, 46, 37 and 48), a symbol sensing slide 4517, a powered sensing slide bail 4519, and a single tooth gear bail 4521. The sensing elements extend transversely across the function plates to sense the depth of opposing surfaces of the active function plate. Each of the sensing elements are connected to other mechanisms of the machine, discussed hereinafter, to carry out operations corresponding to the depth of the surfaces sensed.

Each of the sensing elements 4515, 4517, 4519 and 4521 (FIG. 45) includes a respective cam follower 4523, 4525, 4527 and 4529 which is spring urged into engagement with a corresponding cam surface on the sensing control plate. Movement of the sensing control plate 4235 fully leftward permits each of the sensing elements to ride inward towards the plate to be stopped against an opposing surface of an active function plate. A function plate is released to an active position in the manner discussed hereinbefore, prior to the leftward movement of the sensing control plate.

For example, the accumulator sensing slide 4515 may be stopped by an opposing function plate surface in positions 4515-1, 2, 3, 4 or 5. The lower end of the slide 4515 is bifurcated and engaged with a similar bifurcation formed in the auxiliary keyboard sensing slide 1007 (FIG. 13). As the plate 4235 is moved leftward, the slide 4515 is urged downward in FIG. 45 by a spring 4531, which movement is rightward in FIG. 13, driving the slide 1007 to a corresponding position. As discussed in the "Adding Machine Keys and Mechanism" section hereinbefore, the control slide blocking element 1301 may be driven from the position shown to one of the positions 1301-A-D by the slide 1007 which position corresponds to the position in which the element is blocked by a trip slide (FIG. 6) released by depression of an adding machine control key 201. Likewise, the element 1301 is driven to one of the same positions by the sensing slide 4515 which may be stopped by a corresponding surface on an active function plate. The accumulator register 207 is controlled during the ensuing cycle according to the position of the element 1301. The types of cycles which may be carried out for the positions of the slide 4515 are indicated in FIG. 45 opposite the positions, the cycles being specifically discussed in the "Adding Machine Keys and Mechanism" section.

Likewise, another sensing element, the symbol sensing slide 4517, can be stopped by an opposing function plate surface in positions 4517-X, RM, +, =, =-, Q, T or S to control printing of a X after a multiplier value, RM after a remainder value, a divide sign after a divisor value, an equal sign after a positive multiplicand, an equal minus sign after a negative multiplicand, a Q after a quotient, a T after a total, and an S after a subtotal.

A lever 3021 (FIG. 30) is pivoted at 3023 to the opposite end of the slide 4517. As the sensing control plate 4235 is moved leftward, the symbol slide 4517 is carried upward by a spring 4533 to one of the positions indicated, in which position it is blocked by an opposing surface of an active function plate. The lever 3021 is rocked against the stud 3009, driving the symbol step plate 3003 to a position with a corresponding step opposite the projection 3007 so that the symbol rack 3001 is blocked

against the step upon being driven rightward. The associated printing segment is driven thereby to a position to print the symbol.

5 The powered sensing slide bail 4519 is urged against the sensing control plate by a spring 4535 and can be stopped in any one of seven positions, indicated in FIG. 45, by opposing surfaces of an active function plate. The bail 4519 controls other mechanism to carry out a function or set of functions corresponding to the position of the bail, which mechanism and functions are more fully discussed hereinafter. One important function of this bail is control of the raising and lowering of the multiplier and counter registers 209 and 211 (FIG. 3) into and out of engagement with the single tooth gear 346 and the rack teeth 352 and control of the period of such engagement.

10 The remaining sensing element, the single tooth gear bail 4521, is urged against the plate by a spring 4537 and can be stopped against an active function plate surface at one of four positions indicated in FIG. 45 as 4521-N, 15 CCW, CW and LU. The position in which the bail is stopped controls the direction of rotation of the single tooth gear, i.e. whether the gear is rotated CW, CCW or maintained in neutral, which control is more fully discussed hereinafter.

20 25 At 210°, as indicated on line 39C (FIG. 39), of each cycle, the sensing control plate 4235 is driven rightward by means presently described, held rightward from 240° to 320°, and then permitted to return leftward. During the period that the plate is rightward, the active function plate may be shifted, as discussed hereinafter, in order to 30 present different surfaces to the sensing elements. Initially, unlatching of the sensing control plate 4235 by the master plate 3401 permits a follower 4541 (FIG. 45A), which follower is connected to the plate 4235 by a link 4543, to 35 be rocked CW by a spring 4545. The follower is carried thereby to the position 4541-A and the sensing control plate is moved leftward. Near the end of the first cycle, from 240° to 320°, the cam rises to return and maintain the follower 4541 and the plate 4235 rightward. If the first 40 cycle is a single cycle, either a multiplier entry cycle or a correction cycle, the master plate is returned rightward by means presently described, permitting the latch lever 4505 to re-engage the stud 4511 and latch the sensing control plate rightward. If the first cycle is one of a series of 45 cycles of a multicyclic operation, the sensing control plate follows the cam 4539 and is returned leftward at the end of the cycle with the sensing elements in the sensing positions against opposing surfaces of the active function plate. During the last cycle of a multicyclic 50 operation, the master plate is restored rightward and the sensing control plate 4235 is latched rightward as during a single cycle operation.

Restore of master plate

55 The master plate 3401 (FIG. 44) is restored or driven rightward to permit relatching at the end of a single cycle, i.e. a multiplier entry cycle or correction cycle. It is also relatched at the end of the last cycle of a multicyclic multiplier or division operation. In either case such restoring is accomplished by means of a pair of complementary cams 4901 (FIG. 49) which are keyed to the main shaft 330. The complementary cams 4901 drive a cam follower 4903 every machine cycle, rocking the follower first CW and then CCW. The rise and fall of the 60 complementary cams 4901 are indicated on line 39D (FIG. 39). A stud 4905 extends from the cam follower into engagement with a slot in the right end of a program drive link 4907, forcing the link first leftward and then rightward to the initial position every machine cycle. A hook 4909, which is pivoted to the link 4907 at 4911, is 65 carried leftward with the link every machine cycle. The hook 4909 is spring urged CCW about the pivot 4911 by a spring 4913 between the hook and the link. With 70 the link 4907 in the rightward position shown in the figure, 75 the link 4907 in the rightward position shown in the figure,

a tail 4915 that extends from the hook 4909 is against a frame stud 4917 so that the stud holds the hook in the CW position shown against the CCW urging of the spring 4913.

Normally, a blocking arm 4918 (FIGS. 49 and 49A) underlies a leftward extending nose 4919 on the hook 4909. During cycles of a multicyclic operation, other than the last cycle, the arm 4918 is maintained beneath the nose 4919, preventing the hook 4909 from further CCW rotation throughout the entire cycle. During the last cycle of a multicyclic multiplication or division operation or during a single cycle operation or during a cycle which is not under the control of the program unit, such as an add cycle, the blocking arm 4918 is rocked from beneath the nose 4919, permitting the hook 4909 to rock CCW against an ear 4920. With the link 4907 and hook 4909 driven fully leftward, and with the hook CCW, a shoulder 4921 formed in the hook rises to the position 4921-A to the left of the ear 4920. The ear 4920 is formed on the restore slide 1228 which is held leftward by a spring 4923. During the rightward stroke of the link 4907, the hook 4909, by means of the shoulder 4921, drives the ear 4920 and slide 1228 rightward against the urging of the spring 4923. Another ear 4924 (FIGS. 44 and 49) on the slide 4922, engages shoulder 4425 in the master plate 3401, driving the shoulder from an active position 4425-A to a restore position 4425-B in which the shoulder 4412 is to the right of the ear 4411, permitting the ear to fall to the left of the shoulder.

Near the end of the rightward stroke of the program drive link 4907 (FIG. 49), the tail 4915 engages the frame stud 4917, rocking the hook 4909 CW. The shoulder 4921 is rocked thereby out of engagement with the ear 4920, releasing the slide 4922 and master plate 3401 for movement leftward to respective initial positions. The master plate is latched by the ear 4411 and the slide 1228 stopped against a guide shaft.

The blocking arm 4918 is rocked from beneath the nose 4919 during last cycles and single cycles, for example during a multiplier entry cycle, by means including a carrier stud 4925 (FIGS. 27 and 49). The stud extends through a slot 4926 in the left end of the program drive link 4907, is driven leftward every machine cycle by the link 4907, and is yieldably carried rightward with the link 4907 by means of a spring 4927 connected between the stud and the pivot point 4911 on the link. As the carrier stud 4925 is driven leftward, the carrier 2701, discussed briefly hereinbefore, from which the carrier stud 4925 extends, is driven leftward with the stud. The forward camming edge 2702 engages the stud 2704 which extends from the latching member 2706 that is pivoted to the machine frame at 2736. The member 2706 is cammed CCW thereby, carrying the forward ear 2707 out of engagement with the arm 2709 of the holding bail 2710. This permits the bail 2710 to rock CW to a position 2710-A against the surface 2716 of the multiplier plate 2714. With the holding bail in the position 2710-A, a stud 2737 (FIGS. 27 and 49A) that extends from the nose 2709 is carried CW from the position shown beneath a yielding arm 4928 to a position 2737-A. The yielding arm is mounted on a frame shaft 4929 along with the blocking arm 4918 and is urged CCW about the shaft by a spring 4930. The blocking arm is yieldably held to the yielding arm by a spring 4931. When the stud 2737 is moved to the position 2737-A, the yielding arm 4928 forces the blocking arm 4918 CCW from beneath the nose 4919 of the hook 4909, permitting the hook to rock CCW (FIG. 49) and the shoulder 4921 to engage the ear 4920. At the end of a multiplier entry cycle the master plate 3401 is therefore restored to the rightward position in the manner discussed above.

During a multicyclic multiplication or division, a function plate other than the multiplier plate or correction

plate is leftward in an active position, and when in such a position, other than during the last cycle, a higher surface of the plate is presented to the holding bail 2710 which extends transversely across all of the plates. As for example, surfaces 4704 and 4705 (FIG. 47) of the total plate 4231. Consequently, the holding bail 2710 (FIG. 27) is rocked only partially CW during such cycles, leaving the stud 2737 (FIG. 49A) beneath the yielding arm 4928 so that the nose 4919 of the hook 4909 is prevented from rocking CCW. The nose 4919 therefore rides on top of the blocking arm, preventing the shoulder 4921 from engagement with the ear 4920 on the restore slide. This prevents restore of the master plate 3401. During a last cycle of a multicyclic operation, however, the active function plate is moved to a position in which a lower surface, such as a surface 4706 (FIG. 47) on the total plate, is presented to the holding bail 2710. This permits the stud 2737 to rock to the position 2737-A and the master plate to be restored in the manner discussed.

During other cycles of the machine which are not controlled by the program unit, as for example, a minus cycle, the program drive link 4907 is driven and the holding bail 2710 released every machine cycle in the manner discussed. Since a low surface is presented to the holding bail 2710 the master plate is restored idly, except as discussed hereinbefore in the "Control Key Conditioning Mechanism" section, being driven from the position shown in FIG. 44 to the position 4425-B.

To restore the holding bail 2710 to the position shown, a stud 4427 (FIG. 44) is provided for engagement with an arm 2799 of the holding bail 2710. The stud extends from a bracket 4428 which is riveted to the master plate. As the master plate is restored rightward from 275° to 350° by the program drive link, the stud 4427 engages the arm 2799, rocking the bail 2710 CCW to the position shown in FIG. 27. The latching member 2706 is rocked CW by the other arm 2709 and then is free to rock CCW in front of the arm 2709, latching the bail 2710 in the position shown. The member 2706 and arm 2709 are re-latched during the period that the master plate is moved leftward from the position 4425-B to latch with the ear 4411. The stud 4427 is carried out of engagement with the arm 2709 at this time.

During a multicyclic multiplication or division operation, the active function plate is shifted to the final active position at the end of the next to last cycle. Invariably, shifting to such a position presents a low plate surface to the bail 2710. The bail 2710 is rocked CW thereby against the plate, near the end of the next to last cycle, carrying the stud 2737 to the position 2737-A (FIG. 49A). Since the master plate is not restored during this cycle, means including an ear 4932 (FIG. 49) are provided to maintain the blocking arm 4918 beneath the nose 4919 to prevent the hook 4909 from rocking CCW. As long as the nose 4919 is leftward in front of the ear 4932 during the next to last cycle, the ear is blocked against the side of the nose 4919 (FIG. 49A) from rocking CCW. As the shoulder 4921 is moved rightward of the ear 4920, nose 4919 clears the ear 4932, permitting the blocking arm 4918 to rock from beneath the nose 4919 and the hook 4909 to rock CCW. The master plate therefore is not restored during the next to last cycle even though the holding bail 2710 is rocked against a lower surface. During the next and last cycle, however, the nose 4919 is on the other side of the ear 4932 throughout the cycle, clear of the arm 4918 to permit restore of the master plate.

During a last cycle or a single cycle, the nose 4919 is rocked CCW (FIG. 49), clear of the arm 4918 in the manner discussed. In this position, the nose 4919 prevents the arm 4918 from being rocked CW (FIG. 49A) beneath the nose 4919. However, when the master plate is restored during a last cycle, the stud 2737 is rocked CCW from the position 2737-A to the initial position, driving

the yielding arm 4928 (FIG. 49-A) CW to the initial position. The blocking arm 4918 is prevented from moving with the yielding arm by the nose 4919 until the nose rocks CW (FIG. 49) as a result of engagement of the tail 4915 with the stud 4917. This allows the spring 4931 to move the blocking arm to the initial position underlying the nose 4919.

Multiplier plate

The first action in setting up a multiplication problem is the entry of a multiplier value into the multiplier register 209 (FIGS. 2 and 3) in shortcut form and into the counter register 211 in true form. Such entry is carried out during a single cycle, termed a multiplier entry cycle, of which there are three types, each of which types of cycles are under control of the multiplier plate 2714 (FIG. 27). Every multiplier entry cycle is initiated by depression of the multiplier entry key 110, which depression releases the plate 2714 for movement leftward to one of three active positions: 2714-X_{KB}, 2714-X_A or 2714-X_C, as discussed briefly hereinbefore in the "Control Key Conditioning Mechanism" section. The active position in which the plate 2714 is stopped determines from which one of three corresponding locations in the machine 100 the multiplier value is transferred; from the pin carriage 205, from the accumulator register 207, or from the counter register 211. Prior to depression of the key 110, certain conditions are established which determine the stopping position of the plate 2714.

First, entry of a value into the pin carriage sets up conditions so that the plate 2714 is stopped in the position 2714-X_{KB} after depression of the multiplier entry key, for controlling the machine to carry out a multiplier entry cycle. Such a cycle is termed a keyboard multiplier entry cycle (X_{KB}) during which the value in the pin carriage 205 (FIG. 2) is transferred to the multiplier and counter registers 209 and 211.

Second, with only the subtotal = key 114 depressed and latched down by means discussed before, and without a value in the pin carriage, conditions are set up so that the plate 2714 is stopped in the position 2714-X_A, after depression of the multiplier entry key, for controlling the machine 100 to carry out a cycle, termed an accumulator register multiplier entry cycle (X_A), during which the value in the accumulator register 207 is transferred to the multiplier and counter registers. Depression of a value key 101 after depression of the subtotal = key 114 but prior to depression of the multiplier entry key 110 releases the key 114 from the downward latched position. Thus with a value in the pin carriage, the key 114 can be only idly depressed, as discussed hereinbefore in the "Control Key Conditioning Mechanism" section; consequently, the multiplier plate cannot be preconditioned by both value entry into the pin carriage and depression of the subtotal = key 114.

Third, with no value in the pin carriage and with the subtotal = key 114 in the raised position, conditions are set up to stop the plate 2714 in the position 2714-X_C after depression of the multiplier entry key for controlling the machine 100 to carry out a cycle, termed a counter register multiplier entry cycle (X_C), during which a value stored in the counter register 211 from a previous multiplication or division operation is transferred to the multiplier register.

In each of the three types of cycles, the multiplier value is represented in the multiplier register in short-cut form and in the counter register in true form at the end of the cycle. During the digitation portion of a multiplication operation, discussed hereinafter, the short-cut multiplier value is destroyed during the operation; the true value in the counter register, however, remains as a constant multiplier value for transfer to the multiplier register and for printing during a subsequent X_C multiplier entry cycle.

The multiplier plate 2714 (FIG. 27) is held initially in the nonactive position shown, against the leftward urging of the spring 2726, by an ear 4217 (FIGS. 27 and 42) which is the multiplier keystem 3531 and is in engagement with the shoulder 2724. Depression of the multiplier entry key 110 to initiate one of the three mentioned multiplier entry cycles moves the ear away from the shoulder, releasing the plate 2714 for movement leftward to one of the three corresponding active positions: 2714-A, 2714-B, or 2714-C. Such movement forces the projection 2732 beneath the shaft 4401, raising the shaft and releasing the master and sensing plates to start the motor and engage the main clutch 801 (FIG. 8), in the manner discussed, to initiate a cycle of operation of the machine.

Keyboard multiplier entry cycle (X_{KB}).—Entry of a value into the pin carriage escapes the carriage away from the home order and drives the back latch 4219 (FIG. 41) upward, in the manner discussed in the "Control Key Conditioning Mechanism" section, carrying the ear 4221 to the position 4221-A (FIGS. 41 and 42) in front of the shoulder 2728 (FIGS. 27 and 42). Depression of the multiplier entry key 110, carries the ear 4217 away from the shoulder 2724, releasing the plate 2714 for movement leftward to the position 2714-X_{KB} where the shoulder 2728 is stopped against the ear 4221. With the multiplier plate 2714 blocked in the position 2714-X_{KB}, plate surfaces 2739-X_{KB}, 2740, 2741-X_{KB} and 2742 are opposite the sensing elements 4515, 4517, 4519 and 4521 respectively. The sensing plate 4235 (FIG. 45) is released leftward, in the manner discussed, permitting the sensing elements to fall towards the multiplier plate and to thereby control the calculator 100 to carry out a transfer of the value in the pin carriage to the multiplier and counter registers and to print the symbol X on the tape to the right of the multiplier value.

The accumulator sensing slide 4515 (FIGS. 27 and 45) is stopped against the surface 2739-KB which is at a depth 4515-1 (FIG. 45). At this depth, the slide 4515 leaves the control slide blocking element 1301 (FIG. 13) in the nonadd position as discussed hereinbefore in the Sensing Control Slide portion of the "Program Unit" section. The accumulator register 207 is maintained out of engagement with the racks during both the rearward and forward strokes of the racks as discussed hereinbefore in the Non-add Key portion of the "Adding Machine Keys and Mechanism" section. The accumulator register therefore is not involved in an X_{KB} cycle.

The symbol sensing slide 4517 (FIGS. 27 and 45) is stopped against surface 2740 which is at the depth 4517-X. In this position the slide 4517 (FIGS. 27 and 30) drives the symbol step plate 3003 to a position in which a X step 3025 is opposite the shoulder 3007. As the symbol rack 3001 (FIG. 30A) is driven rightward during the cycle and blocked against the step 3025, the symbol segment is rocked to carry a X symbol to the printing position to print a X following the multiplier value.

The powered sensing slide bail 4519 is stopped against the surface 2741-KB which is at the depth 4519-X_A. In this position the bail 4519 conditions the multiplier and counter register controls 231 (FIG. 2) to maintain the multiplier and counter registers 209 and 211 out of engagement with the racks during the rightward stroke of the racks and to bring the registers into engagement with the racks during the leftward stroke by means discussed hereinafter.

The single tooth gear sensing bail 4521 is stopped against the surface 2714A at a depth of 4521-N (FIG. 45), controlling mechanism discussed hereinafter to prevent the single tooth gear from rotation. The single tooth gear 346 (FIG. 3) is therefore not involved in an X_{KB} cycle.

From the foregoing, an $\times_{KB}$ cycle is initiated by depression of the multiplier entry key 110 with a multiplier value in the pin carriage. During the cycle, the value in the pin carriage 205 (FIGS. 2 and 3) is transferred to the racks 303 when the racks are stopped against the ejected pins 304 during the rightward stroke; the printing segments are rotated to a position to represent the value; the value is printed on the tape followed by a $\times$; the multiplier and counter registers 209 and 211 are brought into engagement with the racks while the racks are rightward; and during the leftward stroke, the multiplier value in the racks is transferred to the multiplier register in short-cut form by means discussed herein-after and to the counter register in true form.

Accumulator register multiplier entry cycle ($\times_A$).—To initiate a $\times_A$ cycle, the subtotal = key 114 is depressed first and latched down; it may, however, already be latched down from an immediately preceding ST = multiplication operation. Then, without entering any value into the pin carriage 205, the multiplier entry key 110 is depressed. This setup calls for transfer of the value in the accumulator register 207 to the multiplier and counter registers 209 and 211 as a multiplier. With the subtotal = key 114 depressed, the keystem 3539 is lowered to a position in which the ear 4143 (FIGS. 27 and 42) is in the position 4143-A, in the path of the shoulder 2730. Since no value is represented in the pin carriage, the backlatch 4219 (FIG. 42) remains in the position shown with the ear 4221 clear of the shoulder 2728. Upon release of the plate 2714, by depression of the key 110 and the ear 4217, the plate is moved leftward past the ear 4221 and is blocked against the ear 4143 in the position 2714- $\times_A$.

With the multiplier plate so blocked, surfaces 2739- $\times_A$, 2740, 2741- $\times_A$ and 2742 are opposite respective sensing elements. The movement of the multiplier plate leftward forced the projection 2732 beneath the shaft 4401, raising the shaft and releasing the master plate 3401 (FIG. 44) and the sensing plate 4235 (FIG. 45) for movement leftward in the manner previously discussed. The sensing elements are released thereby to sense the plate surfaces and control the machine 100 to carry out a transfer of the value in the accumulator register 207 to the multiplier and counter registers 209 and 211.

The accumulator sensing slide 4515 is stopped against the surface 2739- $\times_A$ which is at the depth 4515-5 (FIG. 45), driving the control slide blocking element 1301 (FIG. 13) to the position 1301-A. The accumulator register 207 therefore is brought into engagement with the racks 303 (FIG. 3) during the rightward stroke and then disengaged from the racks during the leftward forward stroke as during a total credit cycle discussed hereinbefore in the "Adding Machine Keys and Mechanism" section.

The symbol sensing slide 4517 is driven against the surface 2740, driving the symbol step plate 3003 (FIG. 30B) to a position in which the step 3025 is opposite the shoulder 3007. As discussed before, the symbol rack is driven rightward and blocked against the step 3025. The symbol segment is rocked thereby to position the $\times$ symbol to print the $\times$ to the right of the multiplier value.

The powered sensing slide bail 4519 (FIG. 27) is stopped against the surface 2741- $\times_A$ as during a $\times_{KB}$ cycle to condition the multiplier and counter register controls 231 (FIG. 2) to maintain the multiplier and counter registers 209 and 211 out of engagement with the racks during the rightward stroke and to bring the registers into engagement with the racks during the leftward stroke.

The single tooth gear sensing bail 4521 is stopped against surface 2714A as during a $\times_{KB}$ cycle, preventing the single tooth gear 346 from rotation. The gear 346 (FIG. 3) therefore is not involved in a $\times_A$ cycle.

From the foregoing, a $\times_A$ cycle is initiated by depression of the key 110 with the key 114 latched down and no value in the pin carriage. During the rightward stroke of the racks 303 the accumulator register 207 is engaged with the racks to thereby transfer the value in the accumulator register to the racks and is then disengaged at the end of the rightward stroke, leaving the accumulator register zeroed. Before the leftward stroke of the racks, the multiplier and counter registers are brought into engagement with the racks so that the value in the racks is transferred into the multiplier register in short-cut form and into the counter registers in true form. The multiplier value is printed with a $\times$ to the right of the value.

Counter register multiplier entry cycle ($\times_C$).—To initiate a $\times_C$ cycle, the multiplier entry key 110 is depressed without a value having been entered into the pin carriage and without the subtotal = key 114 latched down. A $\times_C$ cycle calls for transfer of the true value 20 in the counter register 211 to the multiplier register 209 in short-cut form and printing of the true multiplier value on the tape with a $\times$ to the right of the value.

Since there is no value represented in the pin carriage, the backlatch 4219 (FIG. 42) is in the position shown 25 with the ear 4221 clear of the shoulder 2728 (FIG. 27) of the multiplier plate 2714. Since the subtotal = key 114 is not latched down, the ear 4143 is out of the path of the multiplier plate shoulder 2730. Under these conditions, depression of the multiplier entry key 110 releases the multiplier plate 2714 to move to the full leftward position 2714- $\times_C$ against the shaft 4401. With the plate in this position, surfaces 2739- $\times_C$, 2740, 2741- $\times_C$ and 2742 are opposite respective sensing elements. During the leftward movement of the plate, the projection 35 2732 is forced beneath the shaft 4401, releasing the master and sensing plates for movement leftward in the manner discussed. The sensing elements are released thereby to fall against respective opposite surfaces.

The accumulator sensing slide 4515 is blocked thereby against the surface 2739- $\times_C$ which is at the depth 4515-1 (FIG. 45). At this depth, the control slide blocking element 1301 (FIG. 13) remains in the nonadd position so that the accumulator register 207 is maintained in the neutral position out of engagement with the racks 303. The accumulator register consequently, as during a $\times_{KB}$ cycle, is not involved in a $\times_C$ cycle.

The symbol sensing slide 4517 is stopped against the surface 2740 which is at a depth indicated as $\times$. The symbol step plate 3003 (FIG. 30B) and symbol segment 50 311 are positioned thereby for printing a $\times$ to the right of the multiplier value, as discussed hereinbefore.

The powered sensing slide bail 4519 (FIG. 27) is stopped against the surface 2741- $\times_C$ which is at the depth 4519- $\times_C$ (FIG. 45). At this depth the multiplier and counter register controls 231 are controlled to bring the multiplier register into engagement with the racks on both the rightward and leftward rack strokes and to bring only the counter register into engagement with the racks on the leftward stroke, the counter register being maintained in neutral during the rightward stroke.

The single tooth gear bail 4521 is stopped against the surface 2714A which is at the depth 4521-N. The bail 4521, in this position, prevents the single tooth gear 346 from rotation, which gear therefore is not involved in a $\times_C$ cycle.

It is thus seen that during a $\times_C$ cycle, the counter register 211 (FIG. 3) is brought into engagement with the racks 303 during the rightward stroke of the racks, to stop the rightward movement of the racks in each order when the respective numeral wheels 309 have been rotated to zero. The value in the counter register thus is transferred to the racks. During the leftward stroke of the racks, the multiplier register 209 is brought into engagement with the racks, while the counter register is main-

tained in engagement with the racks. During the leftward stroke of the racks the multiplier value is transferred from the racks back into the counter register in true form and into the multiplier register in short-cut form. The multiplier value is also printed on the tape followed by a $\times$.

Partial and full restore of the multiplier plate.—Near the end of any of the aforementioned multiplier entry cycles, the multiplier plate 2714 is latched in a partially restored position 2714-PR by the following means. At the beginning of a multiplier entry cycle, the holding bail 2710 is released to rock CW, in the manner discussed hereinbefore, against the surface 2716. The stud 2737 (FIGS. 27 and 49A) on the holding bail arm 2709 is moved thereby to the position 2737-A, permitting the yielding arm 4928 and blocking arm 4918 to rock clear of the nose 4919. The hook 4909, therefore, is rocked CCW during the leftward stroke of the program drive link 4907, carrying a shoulder 4933 in the hook to the left of the stud 4925 so that during the rightward stroke of the slide 4907, the stud is engaged and positively restored to the full rightward position. A driving bail 2744 is mounted on a shaft 2745 which is carried by the carrier 2701. The bail is spring urged CW by a spring 2746 mounted on the shaft 2745. One end of the spring bears on a notch in the bail and the other in a cross piece of the carrier. With the carrier 2701 in the normal rightward position shown, a stud 2748 mounted on a right arm of the bail 2744 is forced against a frame member 2749 and is held CCW thereby clear of the plate 2714. As the carrier 2701 is driven leftward by the program drive link 4907 (FIG. 49) as indicated on line 39D (FIG. 39), the driving bail 2744 (FIG. 27) is carried leftward to the position 2744-A. This moves the pin 2748 away from the frame 2749 to permit the spring 2746 to rock the bail CW against a plate surface 2750 which is opposite the bail at this time. A partial restore step 2751 is to the right of the bail. The bail therefore engages the partial restore step during rightward movement of the carrier 2701, driving the multiplier plate rightward slightly beyond a partial restore position 2714-PR. As the carrier 2701 and bail 2744 drive the plate beyond the position 2714-PR, the stud 2748 engages the frame member 2749 and is driven CCW, carrying the bail out of engagement with the partial restore step 2751 and releasing the plate for leftward movement to the partial restore position 2714-PR. The plate 2714 is latched in this position by movement of an ear 2752 on a back latch 4237 (FIGS. 27 and 42) to the left of a shoulder 2753. The sequence and means for moving the back latch 4237 (FIG. 42) upwards to latch the multiplier plate 2714 is as follows.

A spring 4239 urges the back latch 4237 upwards, but the back latch normally is blocked against upward movement by engagement of the ear 2752 with a projection 4240 that extends from a blocking member 4241. The latch 4237 and the blocking member 4241 are shown in positions just prior to depression of the multiplier entry key 110. Depression of the multiplier entry key releases the multiplier plate for movement leftward to one of the three active positions discussed hereinbefore. During such movement, an ear 2742 (FIGS. 27 and 42) on the multiplier plate engages a forward ear 4243 on the blocking member 4241, driving the member leftward with the multiplier plate out of engagement with a detent spring 4244 which normally holds the member 4241 in the position shown. As the blocking member 4241 is moved leftward, the ear 2752 rides upward along the surface 4245 of the projection 4240, under the urging of the spring 4239, until the ear 2752 is stopped

against the side of the multiplier plate. The ear 2752 is engaged normally with a shoulder 4708 (FIGS. 27 and 47) on the total plate 4231 to hold the plate rightward. With the ear 2752 against the side of the multiplier plate, 5 the ear is still engaged with the shoulder 4708 to hold the plate 4231. Similarly, a shoulder 4805 (FIGS. 42 and 48) on the negative plate normally is blocked by an ear 4807, and a shoulder 4605 (FIGS. 42 and 46) on the correction plate 4229 is normally blocked by an ear 4607. With the ear 2752 against the side of the multiplier plate, the negative plate is still blocked by the ear 4807 and the correction plate is still blocked by the ear 4607. A shoulder 4317 (FIGS. 42 and 43) on the division plate 4301, however, normally is not blocked by an ear 4319 and is still clear of the ear 4319 when the ear 2752 is against the side of the multiplier plate. If the multiplier cycle is a $\times_{KB}$ cycle, however, a value was entered in the pin carriage before depression of the multiplier entry key 110, thereby disengaging the ear 4157 (FIG. 42) from the shoulder 4203, in the manner discussed hereinbefore, to permit the division plate 4301 to move leftward to a position in which the shoulder 4307 is blocked by the ear 4309 on the divide keystem 4225. During a $\times_{KB}$ cycle therefore, the back latch 4237 is blocked from rising fully by engagement of the ear 4319 with the side of the division plate as well as the ear 2752 with the side of the multiplier plate.

As discussed previously, the multiplier plate is returned 30 to the partial restore position 2714-PR by the driving bail 2744 near the end of a multiplier entry cycle. As the multiplier plate is driven rightward during a $\times_A$ or $\times_C$ cycle, slightly past the position 2714-PR, the shoulder 2753 is moved rightward of the ear 2752, permitting the ear 2752 to move upward along the surface 4245. The back latch 4237 rises fully thereby, camming the member 4241 leftward, until the lower edge of the slot 4246 is stopped against a guide shaft 4247. With the latch 4237 in the fully raised position, the ear 2752 lies to the left of the shoulder 2753 so that when the stud 2748 (FIG. 27) engages the frame member 2749, the driving bail 2744 is rocked CCW releasing the multiplier plate for movement leftward against the ear 2752. The multiplier plate 2714 is latched thereby in the partial restore position 2714-PR.

During an $\times_{KB}$ cycle, it is necessary to restore the 50 division plate as well as the multiplier plate since the division plate was released leftward upon entry of the multiplier value into the pin carriage. As the driving bail 2744 (FIG. 43) is carried leftward, the bail drops to the left of a step 4320 in the division plate. During the rightward stroke of the bail 2744, the plate is driven rightward to 55 latch the shoulder 4203 (FIG. 42) with the ear 4157 after clearance of the pin carriage permits the back latch 4219 to drop. The shoulder 4317 is clear thereafter of the ear 4319 to permit the back latch 4237 to fully rise. The ear 4319 rises fully to a position opposite the shoulder 4317 60 to prevent the division plate 4301 from movement leftward even though a value is entered into the pin carriage during entry of a multiplicand value. Such entry causes the ear 4157 on the back latch 4219 to disengage the shoulder 4203.

With the back latch 4237 stopped in the fully raised 65 position with the lower edge of the slot 4246 stopped against the guide shaft 4247, ears 2752, 4807 and 4607 are clear of respective shoulders 4708, 4805, and 4605 so that respective plates 4231, 4233 and 4229 are free to move leftward. The total plate 4231 (FIGS. 42 and 47) moves leftward to a position in which a shoulder 4710 is blocked against an ear 4712 on a total = keystem 4714; the negative = plate 4233 (FIGS. 42 and 48) moves leftward to a position in which a shoulder 4809 is blocked

against an ear 4811 on a negative = keystem 4813; and the correction plate 4229 (FIGS. 42 and 46) moves leftward to a position in which a shoulder 4609 is blocked against an ear 4611 on a correction keystem 4615.

After a multiplier entry cycle, with the plates 4231, 4233, and 4229 positioned leftward against ears on respective keystems, a multiplicand normally is entered into the pin carriage; if a zero entry is desired, however, no value keys are depressed, leaving the pin carriage in the home order. In either case, one of a variety of multiplication operations may now be carried out by depression of the T= key 112, the ST= key 114 or the N= key 116, or if a mistake is made in entering the multiplicand, the pin carriage may be cleared by depression of the ST= correction key 105 (FIG. 1) and a new multiplicand entry made before an = key is depressed.

Depression of the subtotal-correction key 105 (FIG. 1) rocks a depending arm of the bail 627 (FIGS. 6 and 46A) CCW, driving a stud 4617, which extends from an arm 4619 (FIGS. 46 and 46A) into engagement with a notch in the correction keystem 4615. The keystem 4615 is driven upward thereby, moving the ear 4611 out of engagement with the shoulder 4609. This releases the correction plate 4229 for movement leftward to an active position to initiate and control a correction cycle, as discussed herein-after, during which cycle the pin carriage is cleared. After such clearance a new multiplicand value may be entered.

When the desired multiplicand is in the pin carriage, a multiplication operation may be initiated by one of the = keys. The following interlocking, however, is provided to prevent more than one program plate from being active at a time. Depression of the total = key 112, drives the total = keystem 4714 (FIG. 42) downward and moves the ear 4712 out of engagement with the shoulder 4710. The total plate 4231 is released thereby for movement leftward to an active position to initiate and control a total = multiplication operation. When the upper edge of the ear 4712 clears the shoulder 4710, the lower edge extends into the path of a shoulder 4621 (FIGS. 46 and 46A) on the correction plate, blocking the correction plate from movement leftward. If the correction key is depressed first, the correction plate is leftward so that the side of the correction plate 4229 blocks the ear 4712 from movement downward while the upper edge of the ear 4712 blocks the total plate 4231. Such an interlocking arrangement prevents the correction plate and total plate from being leftward at the same time.

Interlocking is also provided to prevent the negative plate 4233 (FIG. 42) and the correction plate 4229 from being simultaneously active. Depression of the negative = key 116, drives the negative = keystem 4813 (FIG. 42) downward and the ear 4811 out of engagement with the shoulder 4809, releasing the negative plate 4233 for movement leftward to an active position to initiate and control a negative = total multiplication operation. With the negative = key depressed, the lower edge of the ear 4811 is to the left of a shoulder 4623 (FIGS. 42, 46 and 46A) on the correction plate before the upper edge clears the shoulder 4809. If the correction plate is released leftward before such depression, the lower edge of the ear 4811 is blocked against the side of the plate 4229 while the upper edge still blocks the shoulder 4809, thus preventing the negative plate and correction plate from being leftward at the same time. Neither can the total plate and negative plate be leftward at the same time. An interlock bar 3541 (FIG. 36) is pivoted to the negative = keystem 4813 at 3543 and is spring urged CCW against a frame member 3545. Depression of the negative = key 116 (FIG. 35) drives the keystem 4813 downward by means (not shown) similar to the other keystem arrangement. The bar 3541 is driven leftward thereby to a position in which an ear

3546 engages a notch 3547 in the total = keystem 4714, blocking depression of the total = key 112 when the negative = key is depressed. On the other hand, if the total = key is depressed first, the right edge of the keystem 4714 blocks leftward movement of the ear 3546, preventing depression of the negative = key after depression of the total = key.

Another condition that results from depression of the multiplier entry key 110 involves the ST = key 114. 10 After a multiplier entry cycle, depression of the ST = key drives the subtotal = keystem 3539 (FIG. 36) downward. Since the multiplier entry key 110 is latched in the depressed position as a result of the preceding multiplier entry cycle by means discussed before, a shoulder 3548 in the keystem 3531 is moved to a position 3548-A. When the shoulder 3548 is lowered, an ear 3549 that is urged against the shoulder is moved downward with the shoulder as follows. The ear 3549 is on an arm 3550 which is freely mounted on a frame shaft 3551. The arm 3550 is pivoted to a link 3552 at 3553 and a slot in the right end of the link is engaged with a stud 3554 that extends from a bellcrank 3555, which bellcrank 3555 is mounted on a frame shaft 3556. An interponent 3557 is pivoted to the bellcrank 3555 at 3558 and is urged CW about the pivot by a spring 3559 between the interponent and the bellcrank. When the multiplier entry key is depressed, the shoulder 3548 is lowered to 3548-A; the spring 3559 drives the arm 3550 and the bellcrank 3555 CCW about respective shafts and the link 3552 and the interponent 3557 leftward. An ear 3560 on the left end of the interponent 3557 is carried thereby to a position overlying a shoulder 3561 in the total = keystem 4714. The stud 3537 extends from the subtotal = keystem 3539 over the interponent 3557 so that depression of the subtotal = key 114, after the key 110 is depressed and a multiplier entry cycle is carried out, drives the stud 3537 against the interponent 3557, rocking the interponent CCW and driving the ear 3560 against the shoulder 3561. As a result, the depression of the subtotal = key 114 lowers total = keystem 4714 as well as the subtotal = keystem 3539. The ear 4712 (FIG. 42) therefore disengages the shoulder 4710, releasing the total plate 4231 for movement leftward to initiate and control a subtotal = multiplication operation in the manner discussed herein-after.

After a multiplier entry cycle, depression of the ST= key 114 simultaneously with the N= key 116 does not cause the T= keystem 4714 to be lowered as it is when the ST= key is depressed individually. Simultaneous depression of the ST= key 114 and the N= key 116 drives an ear 3562 (FIG. 36) that is engaged in a notch 3563 in the negative = keystem 4813 downward. The ear is on a bellcrank 3564 which is rocked CW thereby, driving a nose 3565 against the ear 3549 to force the interponent 3557 rightward and the ear 3560 clear of the shoulder 3561. Simultaneous depression of the keystems 3539 and 4813, therefore, does not drive the total = keystem downward. As the keystem 4813 (FIG. 42) is lowered, the ear 4811 is disengaged from the shoulder 4809, releasing the negative plate 4233 for movement leftward to initiate and control a negative subtotal = multiplication operation in a manner discussed herein-after.

After release of one of the program plates leftward to an active position to initiate and control a multiplication operation or a correction cycle, multicyclic multiplication cycles or a single correction cycle are carried out, during which period the multiplier plate 2714 (FIG. 42) remains latched in the partial restore position 2714-PR by the ear 2752 on the back latch 4237. During these cycles, the driving bail 2744 (FIG. 27) is released to rock against a surface of either the total, negative or correction plates, which surface is at least slightly higher than the surface 2750 on the multiplier plate. As a conse-

quence, the driving bail is prevented from engaging a full restore step 2754 of the multiplier plate during these cycles. During the last cycle of a multiplication operation, however, as will be more fully discussed herein-after, either the total plate or negative plate is driven to such a position that a lower surface is opposite the driving bail, permitting the driving bail to rock further CW to the left of the full restore step 2754 as well as similar steps on all of the function plates. During the last cycle, therefore, the multiplier plate and either the total or negative plate, whichever was active are engaged by the bail 2754 and driven rightward to full restore positions. The nonactive function plates are driven rightward to full restore position also but from positions against ears on respective keysystems. In driving the multiplier plate to a full restore position 2714-FR, the ear 2742 is driven to a position 2742-FR. During such movement, the ear 2742 engages an ear 2755, which ear is leftward at this time with the blocking member 4241. The blocking member is driven rightward thereby to the position shown in FIGS. 27 and 42. During such movement, the surface 4245 cams the ear 2752 downward, driving the backlatch 4237 to the position shown with ears 2752, 4807, and 4607 to the left of respective shoulders in the plates 4231, 4233, and 4229, and the ear 4319 clear of the shoulder 4317 in the division plate. The driving bail 2744 is disengaged from the full restore steps of the plates as the stud 2748 (FIG. 27) is moved against the frame member 2749, releasing the total, negative and correction plates for movement slightly leftward to normal positions against respective ears on the backlatch 4237 and the division plate against the ear 4157 on the backlatch 4219.

Correction plate

As discussed in the preceding section, the correction plate 4229 (FIGS. 42 and 46) is provided to enable clearance of the pin carriage upon depression of the subtotal-correction key 105 (FIG. 1) after either a partial or full entry of a multiplicand value. At other times, such as after entry of an addend, depression of the key 105 initiates a correction cycle which is carried out in the manner discussed hereinbefore in the "Adding Machine Keys and Mechanism" section. In the case of a multiplicand, however, the entry of a multiplicand is subsequent to a multiplier entry cycle so that the multiplier entry key 110 is latched in the depressed position in the manner discussed. With the key 110 latched in the depressed position, the left nose of the multiplier key lever 3515 (FIGS. 35 and 36) blocks rightward movement of the interlock bar 3511 and CCW rocking of the bail 703 (FIG. 7). All adding machine keys are rendered ineffective thereby in that release of a corresponding trip slide cannot initiate a machine cycle. The correction plate is necessary therefore as an alternative way of initiating a correction cycle to clear the pin carriage of an incorrect multiplicand.

During a multiplier entry cycle, the correction plate is moved leftward against the ear 4611 in the manner discussed before. Depression of the subtotal-correction key 105 to clear a multiplicand raises the ear 4611 (FIG. 46) on the keystem 4615 out of engagement with the correction plate 4229, releasing the plate for movement fully leftward against the shaft 4405. Such movement forces the projection 4601 beneath the motor starting shaft 4401, raising the shaft to release the master and sensing plates 3401 and 4235 in the manner discussed hereinbefore. Surfaces 4627, 4628, 4629 and 4630 are opposite respective sensing elements 4515, 4517, 4519 and 4521 when the correction plate is fully leftward. The surface 4627 blocks the accumulator sensing slide 4515 (FIGS. 45 and 46) in the position 4515-4, thereby driving the control slide blocking element 1301 (FIGS. 9 and 13) to the position 1301-D to control the machine 100 to carry out a correc-

tion cycle discussed hereinbefore, during which cycle the machine is controlled to maintain the accumulator register 207 out of engagement with the racks 303 and to disable the platen and paper tape feed controls in the manner discussed hereinbefore. The pin carriage, however, is cleared as discussed before.

The surface 4628 conveniently blocks the symbol sensing slide 4517 in the position 4517-S. However, since the printing controls are disabled and no printing is carried out, it makes no difference in which position the slide is stopped.

The surface 4629 blocks the powered sensing slide bail 4519 in the position 4519-N, thereby controlling the multiplier and counter register controls 231 (FIG. 2) to maintain the multiplier and counter registers 209 and 211 out of engagement with the racks 303 during the correction cycle.

The surface 4630 blocks the single tooth gear bail 4521 in the position 4521-N thereby preventing the single tooth gear 346 from rotation.

Near the end of a correction cycle, the correction plate is driven rightward by the program drive link 4907 (FIG. 49) and driving bail 2744 to a position in which the shoulder 4609 (FIGS. 46 and 46A) is to the right of the ear 4611, permitting the ear to move to the latching position shown (FIG. 46A) under the urging of a spring 4632. During a correction cycle the ear 4611 is blocked by the side of the correction plate from movement downward. As discussed before, the program drive link 4907 (FIG. 49) is driven leftward and then rightward each cycle by the cams 4901, thereby driving the carrier stud 4925 (FIG. 49) and carrier 2701 (FIG. 27) leftward also.

As the carrier 2701 moves leftward, the camming surface 2702 engages the stud 2704 on the latching member 2706, rocking the member CW. The ear 2707 is disengaged thereby from the arm 2709, permitting the spring 2712 to rock the bail 2710 CW. Since the correction plate 4229 is fully leftward, a low surface 4634 (FIG. 46) is beneath the holding bail 2710, as well as corresponding low surfaces on all of the other function plates when they are rightward, so that as the bail is rocked CW, the stud 2737 (FIG. 49A) moves to the position 2737-A. The yielding arm 4928 rocks CCW under the urging of the spring 4930, permitting the blocking arm 4918 to rock CCW from beneath the nose 4919 of the hook 4909 which is carried by the program drive link 4907. The hook 4909 rocks CCW into engagement with the carrier stud 4925, forcing the stud rightward during the rightward stroke of the program drive link. The driving bail 2744 (FIG. 27) is mounted on the carrier 2701, is spring urged CW by the spring 2746, and normally is prevented from CW rotation by engagement of the stud 2748 with the frame member 2749. During leftward movement of the carrier, the stud 2748 moves away from the frame member, permitting the spring 2746 to rock the driving bail 2744 CW towards the surfaces of the program plates. With the carrier fully leftward the driving bail is stopped against a surface 4636 on the correction plate 4229 (FIG. 46), which surface is to the left of a partial restore step 4638. During rightward movement of the stud 4925 (FIGS. 27 and 49) and the carrier 2701, the driving bail 2744 engages the partial restore step 4638 and drives the correction plate rightward to the position which permits the keystem 4615 (FIG. 46A) to spring downward to latch the correction plate. The driving bail is rocked CCW upon re-engagement of the stud 2748 (FIG. 27) with the frame member 2749. The surface 4636 (FIG. 46) on the correction plate extends above the surface 2750 (FIG. 27) on the multiplier plate and is opposite the driving bail 2744 under the conditions discussed, thereby preventing engagement of the

bail with the step 2754 and the multiplier plate from being driven rightward with the correction plate.

With the correction plate latched by the ear 4611 (FIG. 46A), a second correction cycle may be initiated to clear a multiplicand by depression of the subtotal-correction key 105 in the manner discussed, any time prior to depression of an = key.

During the last cycle of a multiplication operation, the driving bail 2744 is carried leftward and is permitted to engage a full restore step 4640 on the correction plate in order to drive the correction plate, as well as all function plates, fully rightward to positions in which they may be relatched in the positions shown in FIG. 42 by respective ears on the backlatch 4237.

Total plate

The first step in a total = multiplication operation is to carry out a multiplier entry cycle during which a multiplier value is entered into the multiplier register 209 (FIG. 2) and the counter register 211. The second step is to enter a multiplicand into the pin carriage. Next, the T= key 112 is depressed to release the total plate 4231 (FIGS. 42 and 47) to an active position, in the manner discussed hereinbefore, thereby automatically initiating and controlling a total = multiplication operation which is briefly outlined in the "General Description." As discussed before, the total plate normally is held by the backlatch 4237 (FIG. 42) and is unlatched from this position upon movement of the multiplier plate 2714 to the partial restore position 2714-PR (FIG. 27). Upon release of the total plate 4231 (FIG. 47) by the backlatch 4237, the total plate moves leftward under the urging of a spring 4716 against the ear 4712 on the total = keystem 4714. Depression of the T= key 112 releases the total plate to move leftward to an active position. The side of the plate holds the ear 4712 and the T= key in the depressed position until the plate is restored rightward at the end of the operation.

Referring to FIG. 47, depression of the key 112 lowers the total = keystem 4714 and ear 4712 to release the total plate 4231 for movement fully leftward under urging of the spring 4716 to a P= position in which the right edge of the slot 4703 is against the motor starting shaft 4401. During such movement, the projection 4701 on the plate moves beneath the motor starting shaft 4401 forcing the shaft upwards to release the master plate 3401 (FIG. 44) in the manner discussed hereinbefore, to start the motor and to unlatch the sensing control plate 4235 (FIG. 45) for movement leftward. As the sensing control plate moves leftward, the sensing elements 4515, 4517, 4519, and 4521 ride inward against respective opposite surfaces of the total plate. With the total plate in the full leftward P= position, surfaces 4718-P=, 4720-P=, 4722-P= and 4724-P= are opposite respective sensing elements 4515, 4517, 4519 and 4521.

Print = cycle (P=).—With the total plate in the full leftward P= position, a print = cycle or P= cycle is carried out. One function carried out during such a cycle is printing of the multiplicand value in the pin carriage with an = sign to the right of the value. The accumulator sensing slide 4515 (FIG. 47) is stopped against the surface 4718-P= at the nonadd level 4515-1. The control slide blocking element 1301 (FIGS. 9 and 13A) is not moved thereby but is maintained in the position shown to control the main slides and the calculator to carry out a nonadd cycle during which the accumulator register 207 is kept out of engagement with the racks 303 during both the leftward and rightward strokes of the cycle.

The symbol sensing slide 4517 is stopped against the surface 4720-P= at the level 4517=. The symbol step plate 3003 (FIG. 30) is driven thereby to a position in

which an = step 3027 is opposite the projection 3007 to stop the symbol rack 3001 and symbol segment in a position to print an = sign to the right of the multiplicand value.

5 The powered sensing slide bail 4519 is stopped against the surface 4722-P= at the level 4519-N to thereby maintain the multiplier register 209 and the counter register 211 in neutral positions out of engagement with either the racks 303 (FIG. 3) or the single tooth gear 346 and to disable the pin carriage clearance mechanism in a manner discussed in following sections.

10 The single tooth gear sensing bail 4521 is stopped against the surface 4724-P= at the level 4521-LU, in which position the single tooth gear sensing bail 4521 controls mechanism to latch a countout carriage 6001 (FIG. 55A), which is specifically referred to hereinafter and which carries the single tooth gear 346, to the pin carriage 205. The specific means and manner of such latching also is discussed hereinafter. Generally, however, 15 under the conditions being discussed, the pin carriage is so positioned with respect to the countout carriage after entry of a multiplicand into the pin carriage that the lowest order of the multiplicand is lined up with the single tooth gear 346. After the carriages are latched together, they are released for escapement leftward to a position against a lineup stop 5526 (FIG. 55) in which the lowest order of the multiplicand is lined up with the highest order of the multiplier value in the register 209. The lineup stop is positioned during a multiplier entry 20 cycle by means discussed hereinafter.

25 Summarizing briefly, during the first cycle (a P= cycle) of a total = multiplication operation, under control of the total plate 4231, the racks 303 are driven rightward and stopped against the ejected pins of the pin carriage 30 which represent the multiplicand value. The symbol segment and value printing segments are rotated to positions representative of the multiplicand value so that the value is printed with an = symbol to the right of the value. The racks are then returned leftward, after which the pin carriage and countout carriage are latched together and then escaped to line up the lowest order of the multiplicand and the single tooth gear with the highest order of the multiplier.

30 With the pin carriage, single tooth gear and multiplier register so aligned, the machine is in condition to start multiplication digitation cycles. However, prior to the first digitation cycle, the total plate is shifted to another position in order to control the machine to carry out the first digitation cycle. Such shifting is carried out near the end of the P= cycle after the portions of the P= cycle just discussed. During such first portion, the total plate 4231 (FIG. 47) is in the full leftward position stopped against the motor starting shaft 4401 so that the P= surfaces of the total plate are opposite respective sensing elements. When the program drive link 4907 (FIG. 49) is fully leftward at the period indicated on line 39D (FIG. 39), the driving bail 2744 is in the position 2744-A (FIG. 47). Since the total plate is in the P= position, the driving bail 2744 is to the left of a tooth 4726 which is in the position 4726-P=. Near the end of the P= cycle (line 39D, FIG. 39) the program drive link 4907 is driven rightward, carrying the bail 2744 rightward into engagement with the tooth 4726. The bail drives the total plate to a position D_N in which digitation normal surfaces, D_N, on the total plate are opposite respective sensing elements.

35 Referring to FIG. 39, comparison of lines 39C and 45D shows that the sensing of control plate 4235 (FIG. 45) is driven to the full rightward position prior to shifting of the total plate. The sensing elements are cammed away from total plate thereby, preventing any interference by the sensing elements when the total plate is shifted. After the total plate is shifted, the sensing plate 40

50 55 60 65 70 75 75

With the pin carriage, single tooth gear and multiplier register so aligned, the machine is in condition to start multiplication digitation cycles. However, prior to the first digitation cycle, the total plate is shifted to another position in order to control the machine to carry out the first digitation cycle. Such shifting is carried out near the end of the P= cycle after the portions of the P= cycle just discussed. During such first portion, the total plate 4231 (FIG. 47) is in the full leftward position stopped against the motor starting shaft 4401 so that the P= surfaces of the total plate are opposite respective sensing elements. When the program drive link 4907 (FIG. 49) is fully leftward at the period indicated on line 39D (FIG. 39), the driving bail 2744 is in the position 2744-A (FIG. 47). Since the total plate is in the P= position, the driving bail 2744 is to the left of a tooth 4726 which is in the position 4726-P=. Near the end of the P= cycle (line 39D, FIG. 39) the program drive link 4907 is driven rightward, carrying the bail 2744 rightward into engagement with the tooth 4726. The bail drives the total plate to a position D_N in which digitation normal surfaces, D_N, on the total plate are opposite respective sensing elements.

Referring to FIG. 39, comparison of lines 39C and 45D shows that the sensing of control plate 4235 (FIG. 45) is driven to the full rightward position prior to shifting of the total plate. The sensing elements are cammed away from total plate thereby, preventing any interference by the sensing elements when the total plate is shifted. After the total plate is shifted, the sensing plate

is permitted to return leftward at 320° so that the sensing elements are stopped against the D_N surfaces of the plate at the end of the $P=$ cycle.

In order to discuss the mechanism which enables driving of the total plate to the D_N position, it is necessary to refer back to the action of mechanism in FIG. 49 some of which action occurs earlier in the cycle. As the program drive link is driven leftward, a projection 4934 engages a stud 4916 that extends from a latch lever 4935, driving the lever 4935 CW about a frame shaft against the CCW urging of a spring attached to the stud. An ear 4936 on the upper end of the latch is disengaged thereby from respective tails of four step stops: a 0-step stop 4937, a 1-step stop 4938, a 2-step stop 4939, and a 3-step stop 4940. The individual step stops are mounted freely on a frame shaft 4941 and are urged CCW by respective springs 4942, 4943, 4944 and 4945. At the time that the ear 4936 is disengaged from respective tails of the step stops, the stud 4925, which normally lies beneath the step stops, is leftward, permitting the 1, 2 and 3-step stops 4938, 4939 and 4940 to rock CCW. The 0-step stop 4937 normally is held CW by a link 4946 and during a $P=$ cycle, continues to be so held in a manner discussed later.

During the cycles discussed hereinbefore, involving the program drive link 4907, the hook 4909 is rocked CCW as the tail 4815 is moved leftward from the stud 4917. When the link 4907 is driven rightward during those cycles, the shoulder 4921 in the hook engages the ear 4920 and drives the restore slide 4922 rightward. The ear 4920 extends over the tails of the step stops, rocking the step stops slightly beyond the CW position shown as the slide 4922 is driven rightward, permitting the lever 4935 to rock CCW to relatch the ear 4936 with the step stop tails.

Referring again to the $P=$ cycle, however, with the total plate in the $P=$ position, the holding bail 2710 (FIG. 47) rests against the surface 4705 which is in the position 4705- $P=$. The stud 2737 (FIG. 49A), which extends from the holding bail, remains substantially in the position shown, still in engagement with the yielding arm 4928. The blocking arm 4918 is maintained thereby by beneath the nose 4919 of the hook 4909, preventing the hook from rocking CCW so that during the rightward stroke of the link 4907, the shoulder 4921 is carried rightward without engaging the restore slide 4922. The 1, 2 and 3-step stops 4938, 4939, and 4940, therefore, remain in the CCW position shown, in the path of the stud 4925 which engages the 1-step stop 4937 and is blocked from further movement rightward. As the link 4907 is moved to the full rightward position, the spring 4927 yields and holds the stud 4925 firmly against the 1-step stop. As the stud 4925 is carried to this position, the driving bail 2744 engages the tooth 4726 and drives the total plate from the full leftward $P=$ position to the D_N position, with the surfaces D_N beneath respective sensing elements. The holding bail 2710 drops to the left of a shoulder 4728 which is in a D_N position so that at the end of a $P=$ cycle, the driving bail holds the total plate in the D_N position while the holding bail is just to the left of the shoulder 4728 ready to hold the plate in the D_N position when the driving bail is carried leftward during the next cycle.

First digitation cycle.—At the beginning of the second cycle of a total = multiplication operation, the total plate is in the D_N position and all of the sensing elements are stopped against opposing D_N surfaces. Since the hook 4909 is not rocked CCW for engagement with the ear 4920, the master plate 3401 (FIG. 44) is not restored rightward during a $P=$ cycle. This leaves the main clutch 801 (FIG. 8) engaged and the motor contacts 828 closed so that the second and following cycles follow the first

without further initiation. The accumulator sensing slide 4515 is stopped against a surface 4718- D_N (FIG. 47) which is at the level 4515-3 thereby positioning the control slide blocking element 1301 in the position 1301-B to control the slides 901 (FIG. 9) to carry out a repeat cycle, discussed hereinbefore, during which the accumulator register 207 (FIG. 3) is maintained out of engagement with the racks 303 during each rightward stroke and brought into engagement with the racks during each leftward stroke.

The symbol sensing slide 4517 is stopped against a surface 4720- D_N which is at the level 4517-S. The printing mechanism 214 (FIG. 2), however, is disabled during digitation cycles in a manner discussed hereinafter so that stopping the slide at the level 4517-S is a convenience and has no other meaning.

The powered sensing slide bail 4519 is thus stopped against a surface 4722- D_N which is at a level 4519-2. In this position, the bail controls the multiplier and counter register controls 231 (FIG. 2), in a manner more fully discussed hereinafter, to raise the multiplier register 209 for engagement with the single tooth gear 346 (FIG. 3), to disable the printing mechanism 214 and other functions hereafter discussed, including release of the link 4946 (FIG. 49) to permit the 0-step 4937 to rock CCW for reasons presently described.

The single tooth gear sensing bail 4521 is stopped against a surface 4724- D_N to control the single tooth gear 346 to make one complete CW rotation during each cycle and thereby reduce by one the value in the numeral wheel 307 in which the highest order multiplier digit of the multiplier register is represented, until the value is reduced to zero.

Summarizing, during the first digitation cycle, the racks are driven rightward and stopped against the pins of the pin carriage, the gear 346 reduces or "counts down" the value in the numeral wheel of the highest order of the multiplier value by one, the accumulator register 207 is raised into engagement with the racks 303, and the racks are driven leftward to transfer the value from the pin carriage into the accumulator register. Such digitation cycles are repeatedly carried out until the highest order multiplier digit is reduced to zero, at which time the first partial product is fully developed in the register 207.

More specifically, after the digitation portion of the first digitation cycle from 60° to 170° (line 5A, FIG. 5), the numeral wheel that represents the highest order multiplier digit is sensed to determine whether the wheel is at zero. If the wheel is at zero, the countout carriage and pin carriage are shifted rightward one order to line up the lowest multiplicand order and the single tooth gear with the next lower multiplier order. The order of the 50 multiplier value with which the lowest order of the multiplicand value and the single tooth gear are aligned is hereinafter referred to as the "controlling order." After sensing a zero and shifting, the new controlling order is sensed for a zero, still within the first digitation cycle. If 55 no zero is sensed the sensing control plate 4235 (FIG. 45) is permitted to move leftward near the end of the cycle. If a zero is sensed in the new controlling order, however, the sensing control plate is latched rightward, by means presently described, to prevent release of the 60 sensing elements and to thereby prevent digitation and count down during the second or next cycle since the controlling order is as zero.

Briefly, one of three possible types of digitation cycles are carried out during the first digitation cycle, depending on whether the highest controlling order represents a digit from 2-9, the digit 1 with a value from 1-9 in the next lower multiplier order, or the digit 1 with a 0 in the next lower order. The three types of first digitation cycles 75 and the events associated therewith are summarized in

Table III below, along with second and other digitation cycles. The periods of the cycle during which the events occur are indicated to the left of the table.

TABLE III
TYPES OF DIGITATION CYCLES

A multiplier value which corresponds to column I may be a value such as 4110; column II, 1101; and column III, 1014. In column I, more than one digitation cycle is necessary to reduce the highest multiplier order to zero. In column II only one digitation cycle is required to reduce the highest multiplier order to zero but the next lower order is not at zero. In column III, only one digitation cycle is required to reduce the highest multiplier order to zero, and since the next lower order is at zero, no digitation is carried out during the second cycle.

In the case of column III, to prevent digitation during the second cycle or similar later cycles, a latch 4547 (FIG. 45A) is provided to rock CCW whenever a zero is sensed. Such rocking carries a nose 4549 to a position 4549-A, to the left of an edge 4550 on the sensing control plate 4235 (FIG. 45) to latch the plate rightward during the second cycle. When the pin carriage and countout carriage are shifted rightward, the latch 4547 is rocked CW out of engagement with the plate 4235. During a first digitation cycle of the type in columns II and III, the first zero sensed causes the latch 4547 to rock CCW;

the sensing control plate, however, is leftward at this time (line 39C, FIG. 39) so that the nose 4549 rocks against the side of the plate.

A shift of the carriages occurs at 225° (line 39E, FIG. 39) as a result of sensing a zero at 160°. The latch 4547 is rocked CW as a result of the shift, before the next zero sensing at 290° and before the sensing control plate 4235 is driven rightward at 240°. If a second zero is sensed 60 during the cycle as in column III the latch 4547 again is rocked CCW. At this time, the sensing control plate 4235 is rightward as indicated on line 39C so that the latch rocks to the left of the edge 4550, latching the plate rightward; however, the carriages are not shifted until the shifting period of the next cycle. During the second cycle, the plate 4235 is held latched rightward so that no digitation is carried out, but the second zero is again sensed during the first zero sensing period line 39E, causing the carriage to shift. Such shifting causes the latch 4547 to rock CW while the sensing control plate 4235 is driven rightward by the cam 4539. If a zero is again sensed during the second zero sensing period line of the second cycle, the latch is rocked CCW to again latch the late rightward to prevent digitation during the following cycle; otherwise, if no zero is sensed, the sensing control plate

moves leftward to permit the sensing elements to move against the total plate carry out digitation and count down during the next cycle.

During the second zero sensing period indicated on line 39E (FIG. 39) of every digitation cycle, the controlling order is sensed to determine whether the value contained therein is a shortcut value or a true value. In either case, the driving bail 2744 (FIG. 47) is carried fully leftward and then driven rightward into engagement with a tooth 4730 which is held along with the total plate 4231 in the D_N position by the holding bail 2710. If a true value is sensed, the 0-step 4937 is released CCW by means discussed hereinafter so that the stud 4925 (FIG. 49) is blocked against the 0-step stop and the total plate remains in the D_N position; if a shortcut value is sensed, the 0-step stop is rocked CW so that the stud 4925 is blocked against the 1-step stop and the total plate is driven rightward to a digitation reverse or D_R position. During the leftward stroke of the program drive link 4907, the total plate is held in the D_N position by engagement of the holding bail 2710 with the shoulder 4728. The holding bail remains unlatched and CW throughout the digitation cycles since the carrier 2701 (FIG. 27) does not return rightward but is blocked against one of the step stops.

Throughout a series of D_R cycles, the total plate remains engaged with either the driving bail or the holding bail and reciprocates with the driving bail. The driving bail, however, begins movement leftward after 240° , at which time digitation, line 5A (FIG. 5), is completed and the sensing control plate is rightward so that there is no interference with the sensing elements or digitation functions when the plate is moved.

Digitation reverse cycle (D_R).—When a controlling order is in a shortcut condition, successive digitation cycles are carried out during which the numeral wheels 306 (FIG. 3) are driven by the racks 303 in an opposite or reverse direction from that driven during a D_N cycle. During such cycles the multiplicand value in the pin carriage is successively subtracted from the partial product in the accumulator register a number of times equal to the shortcut value in the controlling order. Prior to each of such digitation cycles the sensing plate 4235 (FIG. 45) moves leftward in the manner discussed to permit the sensing elements to ride inward and sense respective total plate surfaces D_R (FIG. 47). The accumulator sensing slide 4515 is stopped by a surface 4718- D_R at a level which positions the control slide blocking element 1301 (FIG. 13) in the position 1301-C to carry out a minus cycle. The main slides 901 (FIG. 9) are controlled thereby to maintain the accumulator register 207 (FIG. 3) out of engagement with the racks 303 during the rightward stroke of the racks and to bring the accumulator register into engagement with the lower rack teeth 350 during the leftward stroke. The symbol sensing slide 4517 is stopped as a matter of convenience against a surface 4720- D_R at the level 4517-S. However, the printing mechanism 214 is disabled during D_R cycles in a manner discussed hereinafter so that no symbols are printed. The surface 4722- D_R , against which the powered sensing slide bail 4519 is blocked, is at the level 4519-2. In this position the bail 4519 controls the multiplier and counter register controls 231 (FIG. 2) to raise the multiplier register 209 (FIG. 3) for engagement with the single tooth gear 346. The single tooth gear sensing bail 4521 (FIG. 47) is stopped against a surface 4724- D_R at a level 4521-CCW to connect gearing to drive the single tooth gear 346 (FIG. 3) one revolution CCW each cycle, in a manner discussed hereinafter. The single tooth gear therefore drives the numeral wheel 307 in the controlling order one tooth space in the CCW direction each cycle until the numeral wheel is driven to zero in a shortcut direction, i.e., from a value of 5 or greater, to 9. Thus, during each D_R digitation cycle under control of the total plate, the racks are

driven rightward against the detented pins of the pin carriage to represent the multiplicand value; during the leftward stroke of the racks, the accumulator register 207 is lowered into engagement with the lower rack teeth 350 so that the multiplicand value is transferred into the accumulator register 207 subtractively; and the single tooth is driven CCW one tooth space.

After digitation, the controlling order is sensed for zero each cycle as during a D_N cycle, and upon sensing a zero, the pin carriage and countout carriage are shifted to the next lower order. Digitation, sensing, and shifting is carried out in successive lower orders in the manner discussed until the pin carriage is shifted to the home order and digitation carried out in that order until that order is reduced to zero.

Last digitation cycle.—Upon first shifting into the home order, mechanism discussed hereinafter is enabled to initiate a pin carriage clearance and to raise the 0-step stop 4937 (FIG. 49) and the 1-step stop 4938. The step stops are raised when a zero is sensed during the first zero sensing period of the last digitation cycle. Thus, during the last digitation cycle, the pin carriage is cleared and the 0 and 1-step stops raised to permit the total plate to be driven to a total position in which total surfaces T are opposite respective sensing elements. Such driving is the same whether the last digitation cycle is a D_N cycle or D_R cycle.

If the last digitation cycle is a D_N cycle, the total plate 4231 (FIG. 47) is in the D_N position and is held in the D_N position by the holding bail 2710 in engagement with the shoulder 4728 as the driving bail is moved to the leftward position (line 39D, FIG. 39). If the last digitation cycle is a D_R cycle, then during the leftward motion of the driving bail the total plate moves from the D_R position in which it was held by the driving bail to the D_N position where it is held by the holding bail. Thus, not only during the last digitation cycle but during any digitation cycle the total plate is held in the D_N position by the holding bail when the driving bail is moved leftward. As the driving bail 2744 is moved rightward by the program drive link 4907 (line 39D), the driving bail 2744 engages the tooth 4730, driving the total plate rightward until the stud 4925 is stopped against a step stop (FIG. 49). During digitation cycles other than the last digitation cycle, the stud is stopped against either the 0 or 1-step stop. During the last digitation cycle, both the 0 and 1-step stops are raised by means discussed hereinafter so that the stud is stopped against the 2-step stop 4939, thereby driving the total plate further rightward to a total position T in which the total surfaces T are opposite respective sensing elements. At the end of the last digitation cycle, the total plate has been positioned in the T position by the program drive link and driving bail; and the sensing elements (line 39C) are against respective opposite T surfaces of the total plate.

Last multiplication cycle, total cycle.—With the total plate in the T position, the last cycle of a total = multiplication operation is a total cycle such as discussed in the "Adding Machine Keys and Mechanism" section. During the last cycle, the value in the accumulator register (the product) is printed with a red T to the right of the value. With the accumulator sensing slide 4515 (FIG. 47) against a surface 4718-T, the control slide blocking element 1301 (FIG. 13) is in the position 1301-A to block the main slides 901 (FIG. 9) to carry out the discussed total cycle. The symbol sensing slide 4517 (FIGS. 30 and 47) is against the surface 4720-T which is at the level 4517-T, thereby driving the symbol step plate 3003 to a position in which the step 3005 is opposite the projection 3007 on the symbol rack 3001. The symbol segment 311 is driven thereby to a position to print a T to the right of the product. The powered sensing slide bail 4519 is stopped against a surface 4722-T which is at the level 4519-N, in which position the bail controls the multiplier and counter register controls 231 (FIG. 2) to maintain

the multiplier register 209 out of engagement with the single tooth gear 346 (FIG. 3) and to no longer disable the printing mechanism 214. The single tooth gear sensing bail 4521 is against a surface 4724-T which is at the level 4521-N and thereby controls the single tooth gear 346 to remain disengaged from driving mechanism so that the gear does not rotate.

It is seen therefore that during the last cycle of a total = multiplication operation, the accumulator register 207 (FIG. 3) is lowered into engagement with the racks 303 so that during the rightward stroke of the racks, the value in the accumulator register is transferred from the accumulator register to the racks, zeroizing the register. The symbol and printing segments 311 are driven by the racks during the rightward stroke to corresponding symbol and value positions. The plate 327 is then rocked into engagement with segments 311 to complete the printing operation. During the leftward stroke of the racks, the accumulator register is maintained out of engagement with the racks and therefore remains zeroized at the end of the operation.

From 160° to 350° of the last cycle, the program drive link 4907 (FIG. 49) is driven leftward (line 39D, FIG. 39) and then rightward to restore all of the program plates to the normal latched positions. Since the total plate is in the T position, the low surface 4706 is opposite the holding bail 2710, permitting the bail to rock further CW against the surface. Such rocking carries the stud 2737 (FIG. 49A) to the position 2737-A, clear of the yielding arm 4928, to thereby permit the arms 4918 and 4928 to rock CCW and clear of the nose 4919 of the hook 4909. Thus, as the link 4907 moves leftward, the hook 4909 is carried leftward away from the stud 4917 and is rocked CCW by the spring 4913. With the link 4907 fully leftward, the shoulder 4933 engages the stud 4925 and the shoulder 4921 engages the ear 4920. The shoulder 4921 drives the restore slide 4922 rightward during the rightward stroke of the link 4907. The ear 4920 overlies all of the step stops and rocks them CW during the rightward stroke of the link 4907, permitting the stud 4925 to be driven fully rightward during the stroke. The ear 4924 on the restore slide 4922 engages the shoulder 4425 (FIG. 44) and drives the master plate fully rightward to the restore position 4425-B, permitting the ear 4411 to drop to the left of the shoulder 4412 and the latch lever 4505 (FIG. 45) to the left of the stud 4511 on the sensing control plate 4235.

The function plates are driven rightward by the driving bail 744 (FIG. 47). When the total plate 4231 is in the T position and the driving bail 2744 is fully leftward, a low surface 4732 permits the bail to rock further CW than during previous total = multiplication cycles. As the driving bail is carried rightward by the program drive link 4907 (FIG. 49), a step 4734 is engaged and the total plate driven fully rightward. During such rightward movement, the bail next engages the full restore step 2754 (FIG. 27) on the multiplier plate and drives the plates rightward to the full restore position 2714-FR. The backlatch 4237 (FIG. 42) is driven downward thereby by the surface 4245 carrying ears 2752, 4807, and 4607 to latching positions to the left of shoulders 4708, 4805 and 4605 of the total plate, negative plate and correction plate respectively. Prior to movement of the backlatch, all of the plates 4231, 4233, 4229 and 4301 are driven rightward by the driving bail 2744 for relatching: near the end of the rightward stroke, the bail 2744 engages a step 4815 (FIG. 48) on the negative plate 4233, the full restore shoulder 4640 (FIG. 46) on the correction plate 4229 and the step 4320 (FIG. 43) on the division plate 4301. As the stud 4925 (FIG. 49) continues to move rightward, all the program plates, except the sensing control plate 4235 (FIG. 45) which is already rightward, are driven fully rightward to permit the ears on the backlatch 4237 to move to the left of respective shoulders on

the total, negative and correction plates. The division plate 4301 (FIGS. 42 and 43) is driven rightward to permit the ear 4157 to re-engage the shoulder 4203.

As the multiplier plate 2714 (FIG. 27) is driven rightward, a shoulder 2757 (FIG. 27) on the multiplier plate 2714 engages an ear 4248 (FIG. 42) on the latch 4213 and rocks the latch CW. The hook 4211 is rocked thereby out of engagement with the ear 4209 on the latching lever 4209a, permitting the multiplier entry keystem 3531 and the multiplier entry key 110 to rise under the urging of the spring 3527 (FIG. 36). The keystem 3531 rises, carrying the ear 4217 to the position shown to the left of the shoulder 2724 while the multiplier plate is held rightward by the restore slide ear 4924 (FIG. 49).

15 Near the end of the rightward stroke of the program drive link 9407, the tail 4915 engages the stud 4917, the hook is rocked CW out of engagement with the stud 4925 and the ear 4920, releasing the restore slide 4922 for movement leftward. Such release permits the master plate and all of the function plates to move slightly leftward to normally latched positions against respective latching ears. The sensing control plate 4235 (FIG. 42) moves leftward against the latch lever 4505 as the cam 4539 (FIG. 45A) rotates to the normal position at the 25 end of the cycle.

20 Restore of the control plates and function plates to the normally latched positions as described above is carried out during the last cycle of any multiplication or division operation. During single cycle operations, such as an add 25 cycle, the plates are already in the normally latched positions and so are merely driven slightly rightward off respective latching ears and then released leftward against the ears.

Subtotal = multiplication operation

35 A subtotal = multiplication operation is the same as a total = multiplication operation except that during the last cycle the product is subtotalled from the accumulator register 207 (FIG. 3), i.e. the register remains in engagement with the racks 303 during both the rightward and leftward strokes of the racks, and the symbol S is printed to the right of the product. A subtotal = multiplication is initiated by depression of the ST = key 114 (FIG. 1) and is under the control of the total plate 4231 (FIG. 47). 40 Prior to depression of the subtotal = key, a multiplier entry cycle is carried out in the manner discussed hereinbefore, during which the total plate 4231 (FIG. 42) is released leftward to a position in which the shoulder 4710 is against the ear 4712. As presented hereinbefore in the "Multiplier Plate" discussion, depression of the subtotal = key 114, with the multiplier entry keystem 3531 (FIG. 36) latched in the depressed position, drives both the subtotal = keystem 3539, the total = key 112 and total = keystem 4714 downward. Such depression lowers the ear 4712 (FIG. 42) on the total = keystem away from the shoulder 4710 on the total plate 4231, permitting the plate to move leftward to the P = position (FIG. 47). Both keys 112 and 114 are latched down, primarily by the subtotal = key latch 4133 (FIG. 41). 45 The total plate is latched down secondarily by the side of the total plate 4231 (FIG. 42) blocking the ear 4712. The keys 112 and 114 are maintained latched throughout the operation and then released from the latched positions when the program plates are restored during the 50 last cycle in the manner discussed hereinbefore.

55 Depression of the subtotal = key 114 lowers the keystem 3539 (FIG. 42) driving a stud 4250, which is engaged in a slot in the lower end of the keystem, downward. The stud 4250 extends from an arm 4251 which is keyed to the shaft 4207. A second arm 4253 is also keyed to the shaft so that with the stud driven and held downward by the keystem 3559, both arms are rocked and held CCW throughout a subtotal = multiplication operation. The CCW position of the arm 4253 is indicated as 4253-A in FIG. 49 and in this position the arm 4253

is held against a stud 4949 that extends from the 2-step stop 4939. Thus, during the last digitation cycle of a subtotal = multiplication operation, the 2-step stop is held in the CW position clear of the stud 4925. The driving bail 2744 (FIGS. 27 and 47) therefore drives the total plate further rightward and than during a total = multiplication to a subtotal position S instead of T. With the plate in the S position during the last cycle, a surface 4718-S blocks the accumulator sensing slide 4515 in the position 4515-4 and the control slide blocking element 1301 (FIG. 13) in the subtotal position 1301-D (FIG. 9). A subtotal cycle instead of total cycle is carried out during which the accumulator register 207 is maintained in engagement with the lower rack teeth 350 during both the rightward and leftward strokes of the racks 303 so that the product remains in the register at the end of the operation, available for transfer to the multiplier and counter registers 209 and 211 as a multiplier value or to remain in the register 207 for further additions or subtractions. The symbol sensing slide 4517 is blocked against a surface 4720-S in the position 4517-S thereby stopping the symbol step plate in a position with the subtotal step 3011 opposite the projection 3007 in order that the symbol segment is driven to the S position during the last cycle to print an S in red to the right of the product. The powered sensing slide bail 4519 and single tooth gear bail 4521 are blocked against surfaces 4722-S and 4724-S respectively at the levels 4519-N and 4521-N to maintain the registers 209 and 211 in neutral and prevent rotation of the single tooth gear 346 as during the last cycle of a total = multiplication.

Otherwise, a subtotal = multiplication is identical to a total = multiplication: a print = cycle, digitation normal cycles, digitation reverse cycles, a last digitation cycle and restore of the program plates are carried out in the manner presented in the total plate discussion.

Negative plate

The negative plate 4233 (FIGS. 42 and 48) is provided to control the machine to carry out a negative total = multiplication operation or a negative subtotal = multiplication operation, the negative total = multiplication being initiated by depression of the negative = key 116 and the negative subtotal = multiplication being initiated by simultaneous depression of the negative = key 116 and the subtotal = key 110. In either case, prior to such depression a multiplier entry cycle is carried out during which the negative plate 4233 is released leftward and is blocked against the ear 4811. Subsequent depression of the negative = key releases the negative plate to move fully leftward to a print = - (P= -) position in which the right edge of the slot 4803 is against the shaft 4401. The operation of the negative plate is identical in principle to that of the total plate previously discussed. The primary difference between the plates is that a digitation normal surface 4817-D_N on the negative plate is at the level 4515-2 and a digitation reverse surface 4817-D_R is at the level 4515-3 while the corresponding surfaces 4718-D_N and 4718D_R on the total plate 4231 (FIG. 47) are at the levels 4515-3 and 4515-2 respectively. Consequently, the normal digitation cycles carried out during a negative total = multiplication are subtractive and the reverse digitation cycles are additive. The result is that the product is developed negatively. The other difference is that during the first cycle of a negative total = or subtotal = multiplication, i.e. a print = - cycle, the symbol sensing slide 4517 is stopped against a surface 4819 P= - which is at the level 4517= -. The symbol step plate 3003 (FIG. 30) is moved thereby to a position with a step surface 3029 opposite the projection 3007 and the hole 3014 opposite the projection 3019. An = - symbol is printed thereby as indicated in Table II and in the manner discussed hereinbefore in the "Minus Symbol Printing" section.

The driving bail 2744 and holding bail 2710 engage teeth and steps on the negative plate identical to those on the total plate. The bails shift and hold the negative plate in the same manner and under the same controls that the total plate is shifted and held.

The last cycle under control of the negative plate may be either a total credit cycle or subtotal credit cycle. As with the total plate, if the subtotal = key is not depressed, the stud 4925 (FIG. 49) is stopped against the 2-step stop, driving the negative plate to a total position in which total surfaces T are opposite respective sensing elements, which surfaces are at the same level as corresponding T surfaces on the total plate. If the subtotal = key is depressed simultaneously with the negative = key then the arm 4253 (FIGS. 42 and 49) is rocked CCW to hold the 2-step stop raised so that the stud 4925 is stopped against the 3-step stop. The negative plate is driven in this case to a subtotal position in which subtotal surfaces S are opposite respective sensing elements, which surfaces are again at the same level as corresponding S surfaces on the total plate. In either the T or S position, all of the sensing elements are stopped against surfaces of the negative plate at the same level as during a corresponding operation with the total plate. However, since the product is developed negatively in the accumulator register during a negative total or subtotal = cycle, the final value in the accumulator register may be negative. If this occurs, the credit latch 989 (FIG. 9) is rocked CW in the manner discussed in the "Adding Machine Keys and Mechanism" section hereinbefore. As a result, either a total credit cycle or subtotal credit cycle is carried out, rocking the segment 1323 (FIG. 37) to a position in which either the notch 3761-A or 3761-B is opposite the ear 3768. With the segment in either of these positions, as discussed in the "Minus Printing" section a minus is printed during the cycle to the right of the true negative product along with either the symbol T or S.

Division plate

The division plate 4301 (FIG. 43) is provided to automatically control the machine 100 to carry out a division operation. Generally, in setting up a division operation, a dividend value is entered into the accumulator register 207 (FIG. 2) in the manner set forth hereinbefore in the "Dividend Tab Key and Tab Stop Lever" section. A dividend, however, may also be a product in the accumulator register as a result of a previous multiplication or a sum of difference as a result of previous additions or subtractions. In any event, the next step is to enter a divisor into the pin carriage by depression of value entry keys 101 (FIG. 1). Movement of the pin carriage away from the home position as a result of such entry raises the back latch 4219 (FIGS. 41 and 42) from the position in which the ear 4157 blocks a shoulder 4203 of the division plate as discussed hereinbefore in the "Control Key Conditioning Mechanism" section. The division plate 4301 (FIG. 43) is freed thereby for movement leftward under the urging of the spring 4305 to a position in which it is blocked by the ear 4309 (FIGS. 42 and 43) on the divide key 4225.

First division cycle (1st ÷).—With the division plate blocked against the ear 4309, depression of the divide key 118 lowers the ear 4309 away from the shoulder 4307, releasing the plate for movement leftward to a first division (1st ÷) position with the right edge of the slot 4315 against the motor starting shaft 4401. Such movement starts the motor and engages the main clutch 801 (FIG. 8) in the manner discussed before. With the division plate in this position first division surfaces are opposite respective sensing elements to control the machine 100 to carry out a 1st ÷ cycle. The primary functions carried out during the 1st ÷ cycle include clearing the counter register 211 (FIGS. 2 and 3) and setting one of a group of ordinal lineup stops specifically discussed hereinafter, to a blocking position. The order of the lineup stop corre-

sponds to the order of the accumulator register 207 which represents the highest dividend order. During the second cycle of a division operation, the set stop blocks the pin carriage in position in which the highest pin carriage order is aligned with the highest dividend order.

The 1st $\div$ cycle, however, is devoted to the setting of a lineup stop. In order to detect the highest dividend order in the accumulator register, the accumulator register is raised into engagement with the rack teeth 350 (FIG. 3) during the rightward stroke of the racks 303. Only those racks which are engaged with numeral wheels representing the dividend value move rightward; the racks to the left of the highest dividend order are maintained subzero positions by zero suppression means discussed hereinbefore. During the leftward stroke of the racks, but before the racks are fully leftward, the rack to the left of the highest dividend order, which rack is in the subzero position, is sensed and a corresponding lineup stop set.

In order to perform the main function of setting the appropriate lineup stop during the 1st $\div$ cycle, the division plate controls the machine 100 in the following general manner. The accumulator sensing slide 4515 is stopped against a surface 4322—1st $\div$, driving the control slide blocking element 1301 (FIGS. 9 and 13) to the position 1301-D to control the machine 100 to carry out a subtotal cycle in the manner discussed hereinbefore. The symbol sensing slide 4517 is stopped against a surface 4324—1st $\div$ as matter of convenience and is ineffective since the printing mechanism 214 is disabled by other means. The powered sensing slide bail 4519 is stopped against a surface 4326—1st $\div$ at the level 4519-1. At this level the bail 4519 conditions the machine 100 for clearing the counter register 211, for setting the lineup stop during the cycle, and for disabling the printing mechanism. The single tooth gear bail 4521 is stopped against a surface 4328—1st $\div$ which is at the neutral level 4521-N and therefore is not involved in the 1st $\div$ cycle.

Since a value must be entered into the pin carriage in order to enable the divide key 118, at least one ejected pin 304 (FIG. 3) blocks a corresponding shoulder 305 so that the dividend value in the accumulator register may not be entirely transferred to the racks during the 1st $\div$ cycle. However, since the cycle is a subtotal cycle, the value removed from the register during the rightward stroke of the racks is restored intact to the register 207 during the leftward stroke, regardless of the position in which the racks are stopped by the pins during the rightward stroke.

Ordinarily, with the control slide blocking element 1301 (FIG. 9) in the position 1301-D and with a value in the pin carriage, a correction cycle is carried out as discussed hereinbefore in the "Adding Machine Keys and Mechanism" section. As further discussed in that section and in the "Control Key Conditioning Mechanism" section, the control slide latch 915 (FIGS. 9 and 40) normally is rocked CW whenever a value is entered into the pin carriage to enable the main control slide 913 to move leftward clear of the latch ear to a position in which the correction surface 982 is against the control slide blocking element 1301. However, since it is required that a subtotal cycle is carried out during a 1st $\div$ cycle, a first division latch 4330 (FIG. 43) is provided to maintain the control slide latch 915 (FIG. 9) in the CCW position during a 1st $\div$ cycle even though a value is in the pin carriage. As a result, the main control slide 913 engages the latch 915 by means of the shoulder 978 and carries the total slide 977 leftward to a position which the surface 981 is against the element 1301 to control the machine to carry out a subtotal cycle.

The first division latch 4330 (FIG. 43) is slideably mounted on the shaft 4514 and a shaft 4332 and is urged rightward by a spring 4334. In the normal position shown in FIG. 43, an ear 4336 blocks upward movement of a first division link 4338 which is urged upward by a

spring 4340. A first division lever 4342 is connected to the link at 4344 and is mounted for rocking movement on a shaft 4346. The spring 4340 urges the lever 4342 CCW, urging a pin 4347 that extends therefrom into engagement with an ear 4349 extending from the accumulator sensing slide 4515. Upon movement of the division plate to the full leftward position an edge 4351 engages an ear 4353 on the latch 4330, forcing the latch to the full leftward position with the plate. Such movement removes the ear 4336 from blocking the link 4338, releasing the link for movement upward and the lever 4342 for CCW rocking under the urging of the spring 4340. However, the link 4338 and the lever 4342 are blocked from such movement by the ear 4349 until the accumulator sensing slide 4515 is moved downward to sense the surface 4322—1st $\div$. Upon downward movement of the slide 4515, the link 4338 (FIGS. 40A and 43) moves upward in FIG. 43 and leftward in FIG. 40A. As discussed hereinbefore, the lever 4011 is rocked CCW (FIG. 40) upon leftward escapement of the pin carriage after entry of a value therein. Such rocking drives the bellcrank 4021 CCW and the control slide latch 915 upward to the position 915-A. A lever 4033 with a nose 4034 in engagement with a tail 4035 of the lever 4011 is driven CCW by the lever 4011, carrying an arm 4037 to a position 4037-A. Leftward movement of the first division link 4338 during the 1st $\div$ cycle drives a shoulder 4039 against the arm 4037, rocking the lever 4033 CW and the lever 4011 (FIG. 40) CCW. Such rocking permits the bellcrank 4021 to rock CW and drive the latch 915 (FIG. 9) downward to enable the main slide 913 to engage the latch 915 and carry the total slide 977 leftward so that the surface 981 is against the element 1301 to control the machine 100 to carry out a subtotal cycle even though a divisor value is in the pin carriage.

When the sensing control plate 4235 (FIG. 45) is driven rightward near the end of the 1st $\div$ cycle, the element 4515 is driven upward, forcing the ear 4349 (FIG. 43) against the stud 4347. The lever 4342 is rocked CW thereby, driving the link 4338 downward to the position shown. This permits the bellcrank 4021 (FIG. 40) to rock the latch 915 upward and leaves the link 4338 in position for relatching by the ear 4336 upon rightward movement of the division plate 4301 to the next position.

The division plate is driven rightward by the program drive link 4907 (FIG. 49) which is first driven leftward during the 1st $\div$ cycle at the period indicated on line 39D (FIG. 39). With the link 4907 fully leftward and with the division plate fully leftward, the driving bail 2744 (FIG. 43) is carried fully leftward by the stud 4925 (FIG. 49) to a position in which the bail is slightly to the left of a tooth 4354. During the rightward stroke of the link 4907, the bail engages the tooth and drives the plate rightward to a print divide (P- $\div$) position, in which position surfaces 4322 P- $\div$, 4324 P- $\div$, 4326 P- $\div$ and 4328 P- $\div$ are opposite respective sensing elements and the ear 4336 relatches the link 4338.

In order to drive the plate only to the P- $\div$ position, the stud 4925 (FIG. 49) is stopped against the 1-step stop 4938. Normally, the 0-step stop is held CW by means discussed hereinafter and continues to be so held during a 1st $\div$ cycle. The 1, 2, and 3-step stops 4938, 4939 and 4940 rock CCW upon disengagement with the ear 4936 and remain CCW as follows. Since the holding bail 2710 is blocked against a high surface 4355 which is in the position 4355 P- $\div$ when the division plate is in the P- $\div$ position, the stud 2737 (FIG. 49A) remains at 2737-A, beneath the yielding arm 4928 and thereby holds the blocking arm 4918 beneath the nose 4919 (FIG. 49) to prevent the hook 4909 from rocking CCW. The shoulder 4921 therefore cannot engage the ear 4920 to drive the slide 4922 rightward and rock the 1, 2 and 3 step stops CW during the rightward stroke of the link 4907. The stud 4925 therefore is blocked against the 1-step

stop and the division plate driven to the $P \div$ position at the end of the 1st $\div$ cycle.

Another effect of blocking the holding bail 2710 against the surface 4355 is prevention of a pin carriage clearance. As discussed hereinbefore, the holding bail must rock fully CW against a low surface to initiate a pin carriage clearance. Such rocking and clearance is prevented throughout a division operation until a low surface 4356 is opposite the holding bail near the end of a division operation. With the division plate in the $P \div$ position, a high surface is still opposite the bail, preventing a pin carriage clearance.

With the division plate in the $P \div$ position, the holding bail 2710 is to the left of the surface 4355, ready to prevent leftward movement of the plate at the end of 15 the next cycle when the driving bail 2744 is carried leftward.

Near the end of the 1st $\div$ cycle the sensing control plate 4235 (FIG. 45) is released leftward (line 39C, FIG. 39) to permit the sensing elements to move against respective $P \div$ surfaces.

Print divide cycle ($P \div$).—Broadly, the steps carried out during a $P \div$ cycle include the following: first, the divisor value in the pin carriage is printed on the tape 328 (FIG. 3); next the countout carriage, which carries the single tooth gear 346, is latched to the pin carriage so that the single tooth gear is lined up with the lowest divisor order; and finally, the carriages are released for movement leftward to a position in which they are stopped against the lineup stop which was set during the 1st $\div$ cycle. As a result of these steps, the highest orders of the divisor and dividend are aligned.

With the accumulator sensing slide 4515 against the surface 4322 $P \div$, the control slide blocking element 1301 (FIG. 9) remains in the normal position to stop the control slides 901 in a position to carry out a nonadd cycle during which the accumulator register 207 is maintained out of engagement with the racks during the entire cycle. With the symbol sensing slide 4517 against the surface 4324 $P \div$, the symbol step plate 3003 (FIG. 30) is driven to a position in which a step 3031 is opposite the projection 3007 to control the symbol rack 3001 and symbol segment to print the symbol $\div$ to the right of the divisor value. With the powered sensing slide bail 4519 (FIG. 43) against the surface 4326 $P \div$ at a neutral level 4519-N, the multiplier register 209 and counter register 211 are maintained out of engagement with the racks and the printing mechanism 214 remains normally operative. With the single tooth gear sensing bail 4521 against the surface 4328 $P \div$, the bail is at the level 4521-LU. In this position the bail controls mechanism discussed hereinbelow to latch the countout carriage to the pin carriages and then to escape the carriages leftward to a position against the set lineup stop. Thus, during a $P \div$ cycle the divisor is printed, the symbol $\div$ is printed to the right of the divisor, the carriages are latched together and escaped leftward to line up the divisor with the dividend.

During the second half of the $P \div$ cycle, the driving bail 2744 is operated as during a 1st $\div$ cycle discussed hereinbefore and is moved leftward as indicated on line 39D (FIG. 39). The holding bail 2710 holds the division plate 4301 in the $P \div$ position by engagement of the bail with the shoulder to the left of the surface 4355. When the driving bail is fully leftward, the bail is just to the left of a tooth 4357 and engages the tooth when the bail is carried rightward by the carrier stud 4925 (FIG. 49). The division plate is carried rightward therewith. As during a first division cycle the 0-step stop 4937 is maintained in the normal CW position while the 1, 2 and 3-step stops remain in the CCW position. Since the holding bail 2710 (FIG. 43) is blocked against a surface higher than the surface 4356, the hook 4909 (FIG. 49) is blocked by the arm 4918 in the CW position, pre-

venting restore of the step stops during the rightward stroke of the program drive link 4907. The carrier stud 4925 is blocked thereby against the 1-step stop 4938 during the rightward stroke of the program drive link 4907. The division plate 4301 (FIG. 43) is driven by the driving bail 2744 to a digitation normal position (D_N) in which surfaces 4322- D_N , 4324- D_N , 4326- D_N , and 4328- D_N are opposite respective sensing elements. Also, during the second half of the $P \div$ cycle, the sensing control plate 4235 (FIG. 45) is driven rightward as indicated on line 39C (FIG. 39) and then after carrying the sensing elements away from the surfaces of the division plate and after shifting of the division plate from the $P \div$ position to the digitation normal position, the sensing control plate is moved leftward to permit the sensing elements to move against respective D_N surfaces. At the end of the $P \div$ cycle, therefore, the division plate is in the D_N position, the sensing elements are against respective D_N surfaces, ready to control the machine during the next cycle to carry out the first division digitation cycle, which cycle is invariably a digitation normal cycle.

First digitation cycle, digitation normal.—The primary functions carried out during the first digitation cycle include raising the counter register 211 (FIG. 3) for engagement with the single tooth gear 346, carrying out a minus cycle during which the divisor value in the pin carriage is subtracted from the dividend value in the accumulator register 207, and driving the single tooth gear 346 one revolution in the CCW direction, thereby driving the numeral wheel 309 with which the lowest divisor order and the single tooth gear are aligned, which numeral wheel is referred to hereinbelow as the "active wheel." The active wheel is driven one tooth space in the CW direction from the zero position, having been driven to the zero position during the first division cycle during clearance of the counter register.

With the accumulator sensing slide 4515 against the surface 4322- D_N , the slide is at the level 4515-2 (FIG. 45). At this level the control slide blocking element 1301 (FIG. 13) is in the position 1301-C (FIG. 9), in which position with a value in the pin carriage, the minus surface 986 is blocked against element 1301 to control the machine to carry out a minus cycle. As discussed hereinbefore, during a minus cycle, the accumulator register 207 is lowered into engagement with the rack teeth 350 prior to the leftward stroke of the racks, as indicated on line 17E (FIG. 17).

The symbol sensing slide 4517 is blocked against the surface 4324- D_N ; however, the printing mechanism 214 is disabled by other means during all digitation cycles so that the symbol sensing slide is stopped against the surface as a matter of convenience only.

The powered sensing slide bail 4519 is stopped against the surface 4326- D_N which is at the level 4519-4 to control a number of functions. With the bail 4519 in this position, the multiplier and counter register controls 231 (FIG. 2) are enabled to raise the counter register 211 into engagement with the single tooth gear 346; overdraft sensing controls, specifically discussed hereinbelow, are enabled to sense an overdraft in the accumulator register 207; the printing mechanism 214 is disabled; and the 0-step stop 4937 (FIG. 49) is released from the normal CW position to rock CCW.

The single tooth gear bail 4521 is stopped against the surface 4328- D_N which is at the level 4521-CCW. With the bail 4521 in this position the single tooth gear 346 (FIG. 3) is driven one revolution CCW during the first digitation cycle in the manner discussed hereinbelow.

Near the end of the first digitation cycle, the driving bail 2744 is carried leftward in the manner discussed hereinbefore. With the driving bail fully leftward, the bail is just to the left of a tooth 4359. During the leftward stroke of the driving bail 2744, the division plate 4301 is held in the D_N position by engagement of the holding bail

2710 with a tooth 4360. However, since the 0-step stop 4937 (FIG. 49) is released to rock CCW as a result of the powered sensing slide bail 4519 rocking against the surface 4326-D_N, the carrier stud 4925 is blocked against the 0-step stop during the rightward stroke of the program drive link 4907. The driving bail 2744, as well as the stud 4925, are carried rightward therefore by the program drive link only a slight amount before the stud is blocked against the 0-step stop. The division plate therefore remains in the D_N position at the end of the first digitation cycle. The sensing control plate is driven rightward and then permitted to move leftward, as discussed before, so that at the end of the first digitation cycle the sensing elements are again against respective D_N surfaces of the division plate. It is possible however, during the first digitation cycle, that the subtraction will result in an overdraft in the accumulator register. If an overdraft occurs, the overdraft sensing controls, upon sensing an overdraft in the highest accumulator order, momentarily rock the 0-step stop 4937 (FIG. 49) CW out of the path of the stud 4925. Such rocking occurs at the beginning of the second digitation cycle, however, during on overdraft sensing period (line 39E, FIG. 39). If no overdraft occurs during the first digitation cycle, the division plate 4301 (FIG. 43) is maintained in the D_N position during the second digitation cycle so that the divisor value in the pin carriage is subtracted a second time from the dividend value in the accumulator register. Additional subtractions may be carried out in the manner discussed during the first digitation cycle during the second and each successive cycle until an overdraft does occur. At the beginning of the cycle which follows the D_N cycle in which an overdraft does occur, the overdraft sensing controls at the period indicated on line 39E, and more specifically discussed hereinafter, rock the 0-step stop CW out of engagement with the stud 4925, permitting the spring 4927 to carry the stud rightward against the 1-step stop 4938. Since the driving bail 2744 is engaged with the tooth 4359, the division plate is driven rightward with the stud 4925 until blocked against the 1-step stop. The division plate is shifted thereby, at the beginning of the cycle, to a digitation reverse position D_R with surfaces 4322-D_R, 4324-D_R, 4326-D_R, and 4328-D_R opposite respective sensing elements. Although the sensing elements remain against the division plate surfaces during such shifting, there is no interference between the elements and the plate since all D_R surfaces are either at the same level or at a lower level than the D_N surfaces. By delaying the sensing of an overdraft until the beginning of a cycle, a relative long period is available for a carry wave in the accumulator register to actuate the highest accumulator register order. The highest order is sensed each cycle and when actuated, the 0-step stop is rocked CW. After such sensing actuation and shifting, the sensing elements (FIG. 43) are against respective D_R surfaces at the beginning of the cycle to control the machine 100 to carry out a digitation reverse D_R cycle.

Digitation reverse cycle, D_R.—During a division digitation reverse cycle, the divisor value which caused the overdraft is added back to restore the overdraft, and the single tooth gear 346 (FIG. 3) is driven one revolution in the opposite direction to reduce the active order numeral wheel by one.

The accumulator sensing slide 4515 is blocked against the surface 4322-D_R which is at the level 4515-3. At this level the control slide blocking element 1301 (FIGS. 13 and 9) blocks the control slides 901 to carry out an add cycle in the manner discussed hereinbefore.

The symbol sensing slide 4517 is blocked against the surface 4324-D_R which is at the level 4517-S. The slide 4517 is blocked against the surface as a matter of convenience since the printing mechanism 214 (FIG. 2) is disabled by other means during all division digitation cycles.

The powered sensing slide bail 4519 is blocked against the surface 4326-D_R at the level 4519-3. At this level which is the same as during a digitation normal cycle, the counter register 211 is maintained raised for engagement with the single tooth gear 346.

The single tooth gear bail 4521 is blocked against the surface 4328-D_R at the level 4521-CW. At this level, the bail 4521 controls the single tooth gear to be driven one revolution in the CW direction during the D_R cycle.

Thus, during a D_R cycle, under control of the division plate, the divisor value is added to the overdrafted value in the accumulator register, restoring the accumulator register to a positive condition. Also during a D_R cycle, the single tooth gear 346 drives the active order numeral wheel in the counter register one tooth space in the CCW direction, thereby reducing the count in that order by one. At this time the first digit of the quotient is represented by the active numeral wheel in the counter register.

At the time that the overdraft was sensed at the beginning of the D_R cycle, at the period indicated on line 39E (FIG. 39), mechanism for shifting the countout carriage in the pin carriage is enabled as a result of the overdraft to cause shifting of the carriages later in the cycle. Thus, after the digitation portion of a D_R cycle the carriages are shifted at the period indicated on line 39E. The carriages are thus shifted one order to the right, by means discussed hereinafter, to a position in which the highest divisor order is aligned with the second highest dividend of order.

As the program drive link 4907 (FIG. 49) is driven leftward as indicated on line 39D, the driving bail 2744 (FIG. 43) is driven leftward with the link, permitting the division plate 4301 to shift leftward to the D_N position to be blocked by a step 4363 which engages the holding bail 2710. Also, referring to FIG. 49, the 0-step stop 4937 is rocked CCW as the carrier stud 4925 is driven to the left of the step stop. Since the 0-step stop was only rocked momentarily CW upon sensing an overdraft, the step stop rocks CCW at this time, blocking rightward movement of carrier stud 4925. Consequently, during the rightward stroke of the program drive link 4907 the stud 4925 is blocked against the 0-step stop, permitting the driving bail 2744 (FIG. 43) in engagement with the tooth 4359 to drive the division plate only slightly rightward, still maintaining it in the D_N position. The sensing control plate 4235 maintains the sensing elements away from the surfaces of the division plate during such shifting in the manner discussed.

Thus, at the end of the first D_R cycle, the carriages are shifted to the next lower order and the division plate is in the D_N position. During the next cycle a D_N cycle is carried out in the manner discussed hereinbefore. Such digitation normal cycles are carried out until an overdraft occurs, at which time a digitation reverse cycle is carried out and the pin carriages shifted to the next lower order.

During a division operation therefore successive subtractions occur in each order until an overdraft occurs; and upon sensing an overdraft, the divisor is added back into the dividend, a unit value is subtracted from the counter register and the carriages shifted to the next lower order. Such subtractions, addback, sensing and shifting are carried out until the carriages reach the first or home order.

It will be recalled that in multiplication the home order was the order in which the lowest order multiplier value was contained, i.e. the fifth order. In division, however, the home order is the lowest order or the first order. Digitation is therefore carried out through the four lower orders including the home order. Such an arrangement permits the development of a larger quotient value than is possible in conventional machines. The four lower orders are provided in each of the registers 207, 209, and

211 as well as the racks. As specifically discussed later on, the quotient, which invariably extends into the lower four orders, may be transferred to the multiplier register, including the four lower orders for use as a multiplier value. Consequently, the last digitation cycle of a division operation is carried out in the first order, which order is also referred to hereinafter as the home order.

Last digitation cycle.—Digitation is carried out in the home order in the same manner as in other orders as discussed hereinbefore. However, upon shifting into the home order, mechanism, specifically discussed hereinafter, is enabled so that upon sensing an overdraft, the mechanism rocks the 1-step stop 4938 (FIG. 49) CW following the digitation portion of the D_R cycle. Also, during the last digitation cycle, following the digitation portion of the cycle the pin carriage and countout carriage are disengaged. The pin carriage is then cleared in the manner discussed hereinafter, even though the holding bail 2710 (FIG. 43) rests against a high surface. The countout carriage maintains the single tooth gear 346 in the lowest order, available for a multiplication operation and it does not move from the first order to the fifth order except during a multiplication operation, until the counter register is cleared.

During the portion of the last cycle during which the program drive link 4907 (FIG. 49) is moved leftward, the division plate is held in the D_N position by the bail 2710 against the tooth 4360. At this time both the 0 and 1-step stops are rocked CW so that upon the rightward stroke of the program drive link the stud 4925 is carried rightward by the spring 4927 until it is blocked against the 2-step stop 4939. Such rightward movement of the stud 4925 carries the driving bail 2744 (FIG. 43) rightward into engagement with the tooth 4359, driving the division plate 4301 rightward to a print quotient (PQ) position in which surfaces 4322-PQ, 4324-PQ, 4326-PQ and 4328-PQ are opposite respective sensing elements.

Print quotient cycle (PQ).—In the manner discussed before, the sensing elements are removed from engagement from the surfaces of the division plate near the end of the last digitation cycle while the plate is shifted to the PQ position and are then released against the plate.

With the accumulator sensing slide 4515 against the surface 4322-PQ, the blocking element 1301 (FIGS. 9 and 13) blocks the control slides 901 to carry out a non-add cycle during which the accumulator register is maintained out of engagement with the racks.

The symbol sensing slide 4517 is blocked against the surface 4324-PQ at the level 4517-PQ. With the slide 4517 in this position the symbol step plate 3003 (FIG. 30) is driven rightward to a position in which a Q-step 3033 is opposite the projection 3007 thereby blocking the symbol rack 3001 and the symbol segment 311 in a position to print the symbol Q.

The powered sensing slide bail 4519 is blocked against the surface 4326-PQ at the level 4519-4. With the bail at this level, the counter register 211 (FIG. 3) is lowered into engagement with the rack teeth 352, prior to rightward stroke of the racks and is maintained in engagement with the racks throughout the rightward and leftward strokes. The single tooth gear sensing bail 4521 is blocked against the surface 4328-PQ at a neutral level and therefore does not enter into this operation.

Thus, during a PQ cycle, the quotient value developed during the digitation cycles is transferred by means of the racks to the printing segments, the quotient value is printed on the tape 328 with the symbol Q printed to the right, and then the quotient value is transferred from the racks to the quotient register available for use as a multiplier value.

When the 0-step stop 4937 is rocked CW at the beginning of the last digitation cycle it is maintained in the CW position through the remainder of the division operation. Also, during the last digitation cycle the 1-step stop 4938 is released from the CW position to which it was

rocked in order to enable the division plate to be driven to the PQ position, so that at the end of the last digitation cycle the 1-step stop is CCW.

Following the rightward and leftward strokes of the racks, the program drive link 4907 is driven leftward carrying the stud 4925 and the driving bail 2744 to the full leftward position. The 0-step stop remains latched in the CW position in which it was latched during the last digitation cycle while the 1-step stop is free to rock CCW. During the rightward stroke of the program drive link the driving bail 2744 engages the step 4320, driving the division plate rightward to a remainder (RM) position at which the stud 4925 engages the 1-step stop. During the leftward stroke of the program drive link, the division plate 4301 was held in the PQ position by engagement of the holding bail 2710 with a tooth 4361. During the period that the plate is shifted from the PQ to the RM position the sensing control plate cams the sensing elements away from the division plate and then releases them for movement against the plate, so that at the end of the PQ cycle the division plate is in the RM position in which surfaces 4322-RM, 4324-RM, 4326-RM and 4328-RM are opposite respective sensing elements.

Print remainder cycle (RM) or last division cycle.—During the last division cycle the remainder value in the accumulator register is printed on the tape 328 with an RM printed to the right of the value; and the accumulator register and the division plate as well as the master plate and all of the other program plates are restored to the normal positions.

With the accumulator sensing slide 4515 against the surface 4522-RM the control slide blocking element 1301 (FIGS. 9 and 13) blocks the control slides 901 in a position to carry out a total cycle discussed hereinbefore.

The symbol sensing slide 4517 is against the surface 4324-RM at the level 4517-RM thereby driving the symbol step plate 3003 to a position in which an RM step 3035 is opposite the projection 3007 on the symbol rack 3001 so that as the symbol rack is driven rightward it is blocked against the step 3035, rocking the symbol printing segment to a corresponding position to print the letters RM after the remainder value.

The bails 4519, 4521 are blocked against respective neutral surfaces 4326-RM and 4328-RM which are at neutral levels and therefore do not enter into this operation.

As the program drive link 4907 moves leftward near the end of the RM cycle the carrier stud 4925 and driving bail 2710 are carried to full leftward positions. The holding bail 2710, however, engages the step 4363, holding the division plate in the RM position. The division plate, when driven to the RM position at the end of the PQ cycle is in a position with the step 4363 to the right of the holding bail 2710. At this time the holding bail 2710 rocked CW against the low surface 4356. Thus, during the leftward stroke of the program drive link, the hook 4909 rocks fully CCW since the stud 2737 (FIG. 49A) on the holding bail is rocked to the position 3727-A.

The blocking arm 4918 is rocked clear of the hook nose 4919, permitting the hook to rock CCW under the urging of the spring 4913 as the tail 4915 moves away from the frame stud 4917. During the rightward stroke of the program drive link 4907 the hook shoulder 4921 engages the ear 4920 on the restore slide 4922, driving the slide rightward and all of the step stops CW during the rightward stroke of the link. As discussed hereinbefore, the driving bail 2744 engages the step 4320, as well as similar steps on the other function plates, and drives the plates fully rightward for latching by respective ears on the backlatch 4237 (FIG. 42). The rightward driving of the restore slide 4922 restores the master plate 3401 (FIG. 44) in the manner discussed hereinbefore so that the master plate and the sensing control plate 4235 (FIG. 45) are latched in normal positions thereby disengaging

the main clutch 801 (FIG. 8) and disconnecting power to the motor. This concludes the division operation. At such conclusion the counter register still contains the quotient value which is available for transfer to the multiplier register as a multiplier value, while the accumulator register is cleared as a result of the total operation during which the remainder value was printed.

Square Plate

The nature of the program unit is such that additional plates may be added to the unit for control of the machine 100 to carry out other operations such as $A + (B \times C \times D \times E \dots)$ or $\times^n$. Alternatively, the function plates discussed may be replaced by other plates to carry out functions other than those discussed. For example, a square plate 5000 (FIG. 50) may be added as an extra plate to the program unit, or the negative plate 4233 (FIG. 48) may be removed from the program unit and the square plate assembled in its place. If the square plate is added as an extra plate a new key is needed for control of the plate; however, if the square plate is assembled in place of the negative plate, the negative = key 116 may be used for control of the square plate and a new symbol placed on the key top. In FIG. 50, the square plate is assembled in place of the negative plate so that the ear 4811 on the negative = keystem 4813 (FIG. 42) blocks a shoulder 5001.

The operation carried out under control of the square plate is a combination of a keyboard multiplier entry cycle, as carried under control of the multiplier plate, and a total = multiplication operation as carried out under control of the total plate. In a squaring operation, the value to be squared is entered at the keyboard into the pin carriage. The square key (negative = key 116) is then depressed. Such depression initiates the squaring operation during which the value in the pin carriage is entered into the multiplier register 209 and then a total = multiplication operation carried out. During such operation, the value in the multiplier register and the value in the pin carriage register are used to develop a product in the accumulator register which is totaled out of the register at the end of the operation.

Upon depression of the square key, the ear 4811 moves away from the shoulder 5001 to permit a spring 5002 to carry the plate 5000 leftward to a position in which the right edge of a slot 5003 is against the motor starting shaft 4401. Such movement releases the master plate and sensing plate to start the motor and engage the main clutch, in the manner discussed hereinbefore, and to position the plate with surfaces $\times_{KB}$ opposite respective sensing elements. Since the $\times_{KB}$ surfaces on the square plate 5000 are the same as the corresponding surfaces on the multiplier plate 2714 (FIG. 27), a keyboard multiplier entry cycle is carried out as described in the multiplier plate discussion hereinbefore. During the $\times_{KB}$ cycle, the bail 2710 is rocked against a surface 5004 of the square plate which is not a low surface so that the machine continues to cycle and the pin carriage is not cleared. As a result, the driving bail 2744 engages a step 5005, driving the plate rightward to a print = (P=) position in which the carrier stud 4925 (FIG. 49) is blocked against the 1-step stop.

The P= surfaces on the square plate 5000 are identical with the corresponding surfaces on the total plate 4231 (FIG. 47) as well as the remaining surfaces D_N , D_R , and T. The remaining steps and teeth opposite respective bails 2710 and 2744 are also identical to those on the total plate. As a result, the remainder of the operation is identical to the total = multiplication operation described in the total plate discussion except that the square plate is restored at the end of the operation to a position in which the shoulder 5001 is blocked against the ear 4811.

MULTIPLIER AND COUNTER REGISTER CONTROLS

Multiplier and counter register controls 231 (FIG. 2) are provided to lower the multiplier register 209 and counter register 211 into engagement with the rack teeth 352 (FIG. 3), to raise the multiplier and counter registers to positions for engagement with the single tooth gear 346, and to centralize the multiplier and counter registers.

The main elements of the controls 231 are a powered sensing slide 5101 (FIG. 51), an early slide 5201 (FIG. 52) and a late slide 5301 (FIG. 53).

Generally, the early and late slides are responsive to the position of the powered sensing slide to move the multiplier register and the counter register to positions called for by the program plate surface against which the powered sensing slide 4515 (FIG. 45) is stopped.

Powered Sensing Slide

The powered sensing slide 5101 is driven leftward every machine cycle by a cam 5103 (FIG. 51A) which is keyed to the main shaft 330. During such movement the powered sensing slide is blocked in one of six positions by an ear 5105 on a powered sensing slide blocking lever 5106, or is driven to a seventh position fully leftward if the ear is clear of the slide. The ear 5105 is carried to one of the seven positions by engagement of the lever 5106 with an ear 5108 on the powered sensing slide bail 4519 (FIG. 45). The bail 4519, in turn, during a cycle of a multiplication or division operation, is blocked against a surface of a program function plate at one of the levels 4519-N, $\div 1$, $\times_A$, $\times_C$, $\div 4$, $=2$ or $\div 3$. The ear 5105 therefore is carried to a corresponding position 5105-N, $\div 1$, $\times_A$, $\times_C$, $\div 4$, $=2$ or $\div 3$ to block the slide 5101. During cycles other than multiplication or division cycles, the sensing control slide 4235 is latched rightward, holding the bail 4519 in the position shown and the ear 5105 in a corresponding position 5105-N. During such cycles and during multiplication and division cycles in which the bail 4519 is blocked at the level 4519-N, the powered sensing slide 5101 is blocked by means of a step 5138 in a neutral position against the ear 5105 in substantially the position shown in FIG. 51 and does not enter into the operation.

In any case, the powered sensing slide is urged leftward by CCW rotation of the cam 5103 every machine cycle. During such rotation, a drive cam follower 5109 is rocked CCW about a shaft 5111, against a spring 5110. A stud 5112 on the follower is in engagement with a slot 5113 in a lever 5114 to drive the lever CW about a shaft 5115. A stud 5116 on the lever 5114 is driven CW thereby against a driving arm 5118 which is loosely mounted on a shaft 5119, forcing the arm 5118 CCW. A yielding arm 5121, which is also keyed to the shaft 5119, is connected to the driving arm through a spring 5122 so that as the driving arm is forced CCW, the yielding arm follows, rocking the shaft 5119 CCW. A driving member 5124 is keyed to the shaft 5119 and is in engagement with a stud 5125 on the powered sensing slide. Thus, as the cam 5103 is driven CCW the member 5124 is rocked CCW with the yielding arm to yieldably drive the powered sensing slide leftward. If the ear 5105 is in one of the first six positions, the powered sensing slide is stopped against the ear. After such blocking the cam 5103 continues to drive the driving arm 5118 CCW; however, the member 5124, the yielding arm 5121, and the powered sensing slide 5101 are blocked from movement. The spring 5122 therefore yields as the cam follower 5109 continues to rise. When the ear 5105 is in the position 5105- $\div 3$, the powered sensing slide misses the ear 5105 altogether and is driven fully leftward to the full rise of the cam. The motion of the cam 5103 is indicated on line 54A (FIG. 54).

Early slide

The early slide 5201 (FIG. 52) may be used to raise either the multiplier register 209 or the counter register 211 for engagement with the single tooth gear 346 (FIG.

3); or the early slide may lower the counter register into engagement with the rack. In either case, and at the end of the periods of such engagement, which may extend over several cycles in the case of engagement with the single tooth gear, the registers are centralized by the slide.

Provision is made to reciprocate the early slide normally rightward and then leftward every machine cycle. Such reciprocation is accomplished by means of a gear 5202 which is mounted loosely on an auxiliary cam line shaft 5203 and is continuously engaged with a gear 5204 that is keyed to the main shaft 330. Both cams make one complete 360° revolution every machine cycle. A single tooth ratchet gear 5206 is integral with the gear 5203 and also rotates 360° every machine cycle. A clutch disk 5208 is keyed to the shaft 5203 and carries a clutch pawl 5210 pivoted thereto at 5212. The pawl is urged into engagement with the gear 5206 by a spring 5214 mounted between a hole in the end of the clutch pawl and a stud on the disk. Since the clutch disk 5208 is keyed to the auxiliary cam line shaft 5203 and the clutch pawl 5210 is held normally in engagement with the ratchet gear 5206, the auxiliary cam line shaft normally rotates 360° each machine cycle. During such rotation, a cam 5216, which is keyed to the auxiliary cam line shaft 5203, reciprocates a cam follower 5218 first CCW and then CW about a shaft 5220. As the cam follower 5218 rocks CCW and then CW, a slot 5222 in the follower forces a stud 5224 on an early slide driver 5226 CW and then CCW about the shaft 5115. Another stud 5228, also on the driver 5226, is mounted in a slot 5230 in the early slide 5201. The early slide 5201 therefore is reciprocated normally rightward and then leftward every machine cycle. The rise and fall of the cam 5216 and therefore the periods of reciprocation of the early slide 5201 is indicated on line 54B (FIG. 54).

Multiplier register raised for engagement with the single tooth gear (STG).—An early M hook 5232 (FIG. 52) is pivoted on the early slide at 5234 and is urged CW by a spring 5236 between the early hook and the early slide. The hook is stopped against a stud 5238 on the early slide. During a D_N or D_R cycle of a multiplication operation, a stud 5127 (FIGS. 51 and 52) on the powered sensing slide 5101 rocks the early M hook CCW so that the multiplier register 209 (FIG. 3) is raised for engagement with the single tooth gear 346 as explained below.

Referring to FIG. 47, when the total plate 4231 is driven to the D_N or D_R position, the powered sensing slide bail 4519 is rocked against either the surface 4722- D_N or 4722- D_R both of which surfaces are at the level 4519=2, thereby rocking the ear 5105 (FIGS. 45 and 51) to the position 5105=2. During either a D_N or a D_R cycle, the powered sensing slide 5101 is moved leftward to a position in which a step 5129 is blocked against the ear 5105. With the slide in this position, the stud 5127 is in a position 5127=2 (FIG. 52) in which the early M hook 5232 is formed and held in a CCW position 5232=2. A hook 5240 is engaged thereby with a stud 5242 which is on a lever 5130 (FIG. 51), which lever is loosely mounted on a shaft 5132. Another stud 5133 on the lever 5130 is engaged in a slot in an arm 5135 which is keyed to a multiplier register box cam shaft 5136 (FIGS. 51 and 55). A pair of right and left multiplier register box cams 5501 are keyed also to the shaft 5136 only the left cam being shown in FIG. 55. A camming slot 5502 in each box cam is engaged with a roller on right and left multiplier register end plates 5504 which are mounted for vertical movement as follows. Each end of the multiplier register shaft 312 is engaged with a slot 5505 in respective right and left side frames 5507 and extends through the slot into engagement with respective end plates 5504. A stud 5508 extends from the upper end of each end plate into engagement with a slot 5509 in the side frame. Thus, with the powered sensing slide step 5129 (FIG. 51) blocked against the ear 5105 and

the early M hook 5232 engaged with the stud 5242, the lever 5130 is rocked CCW, as the early slide 5201 (FIG. 52) is driven rightward by the cam 5216 during the period indicated on line 54B (FIG. 54). Counterclockwise rotation of the lever 5130 rocks the shaft 5136 and the box cam 5501 (FIG. 55) CW, forcing the end plates 5504 and the shaft 312 upward to a position 209-A for engagement with the single tooth gear 346 during D_N and D_R multiplication cycles.

If the powered sensing slide 5101 (FIG. 51) is blocked in any of the positions other than the =2 position, the stud 5127 (FIG. 52) does not hold the early M hook 5232 CCW. The hook 5240 therefore does not engage the stud 5242 or affect the multiplier register during rightward movement of the early slide 5201.

When the powered sensing slide 5101 (FIG. 51) is driven to the =2 position during the first multiplication digitation cycle, a latch 5137 is urged by a spring 5138 into a notch 5139 in the powered sensing slide, preventing the slide from returning rightward until the conclusion of digitation. This prevents repetitive reciprocation of the powered sensing slide and the early slide, which in turn prevents repetitive raising and lowering of the multiplier register 209. The multiplier register therefore is maintained raised for engagement with the single tooth gear 346 until digitation is concluded by the following means. A lever 5243 (FIG. 52A) is keyed to the shaft 5119, through which shaft force is transmitted to move the powered sensing slide leftward (FIG. 51A). A stud 5244 (FIG. 52A) on the end of the lever 5243 assumes positions corresponding to the positions in which the powered sensing slide is blocked. When the powered sensing slide is blocked in the =2 position, the stud is in a position 5244=2.

During such movement to the position 5244=2, the stud 5244 drives against a clutch dog latch 5246, rocking the latch CW. A nose 5248 is moved thereby away from latching engagement with a clutch dog bail 5250 to permit the bail to rock CW about the shaft 5220, under the urging of a spring 5252, into the path of a tail 5254 of the clutch pawl 5210. After the tail 5254 and disk 5208 rotate approximately 180°, the tail 5254 engages the clutch dog bail 5250, rocking the clutch pawl 5210 CCW about the pivot 5212. The pawl is disengaged thereby from the gear 5206 which is integral with the gear 5202. The clutch disk 5208 is centralized by a centralizer 5256 which is spring urged into a notch on the clutch disk 5208 to maintain the disk in the centralized position after disengagement of the pawl from the gear 5206. At the period of such disengagement, the early slide 5201 is fully rightward (line 54B) and is maintained rightward therefore through all of the multicyclic digitation cycles of a multiplication operation. When a zero is sensed during the first zero sensing period (line 39E, FIG. 39) of the last multiplication digitation cycle, the clutch dog bail 5250 is rocked CCW, in a manner discussed specifically hereinabove, out of engagement with the clutch pawl tail 5254 to permit the pawl tail 5254 to permit the pawl to re-engage with the ratchet wheel 5206. Since the pawl is released at 180° (line 39E) prior to the time that the ratchet rotates to the 180° position, the ratchet gear 5206 engages the clutch pawl 5210 at 180° of the machine cycle, driving the auxiliary cam line shaft 5203 through the remaining 180° as the cycle is completed.

A stud 5141 (FIG. 51), which is on a disk 5143 that is keyed to the shaft 5203, rotates with the disk. During the first digitation cycle, the disk and stud 5141 are stopped in a 180° position 5141-A when the pawl 5210 is disengaged from the gear 5206. Consequently, upon re-engagement of the pawl and gear during the last digitation cycle, the stud is driven CW from the position 5141-A to the normal position. During such rotation, the stud 5141 engages a camming surface 5144 and rocks the latch 5137 CCW. The latch is disengaged thereby from the notch

5139, releasing the powered sensing slide for movement rightward by the spring 5110 (FIG. 51A).

After re-engagement of the clutch pawl 5210 (FIG. 52A) with the ratchet gear 5206, the cam 5216 rotates the second 180° (line 54B, FIG. 54), driving the early slide 5201 (FIG. 52) leftward. As a result, a centralizing surface 5258 is driven against the stud 5242 rocking the lever 5135 (FIG. 51) and the box cam 5501 (FIG. 56) CCW to the position shown, thereby lowering the multiplier register 209 (FIG. 55) away from the single tooth gear 346 to the centralized position.

Counter register raised for engagement with single tooth gear (STG).—At the end of a P $\div$ cycle of a division operation, just prior to a first digitation cycle, the powered sensing slide bail 4519 (FIG. 43) is blocked in the position $4519 \div 3$ against the surface 4326-D_N of the division plate. The ear 5105 (FIG. 51) is carried thereby to a position $5105 \div 3$, clear of the powered sensing slide 5101. During the first digitation cycle of a division operation, the powered sensing slide is moved fully leftward and is 20 blocked against guide shafts 5115 and 5132, carrying a stud 5260 (FIGS. 51 and 52) to a position $5260 \div 3$. An early C hook 5261 is pivoted on the early slide at 5262 and is engaged by the stud 5260 as the stud is moved to the position $5260 \div 3$, forcing the hook CCW against a spring 5263. With the hook 5261 in the CCW position, a hook portion 5264 is in a position 5264-A, engaged with a stud 5265 on a lever 5145 (FIG. 51) which is loosely mounted on the shaft 5115.

Consequently, as the early slide 5201 is driven rightward, the hook portion 5264 engages the stud 5265 and rocks the lever 5145 CCW. Another stud 5146 on the lever 5145 is engaged with a slot in an arm 5147 which is keyed to a counter register box cam shaft 5148. As the stud 5265 is driven rightward, the shaft 5148 (FIGS. 51 and 55) is rocked CW. A left counter register box cam 5511 and a right box cam 6700 (FIG. 67) are keyed to shaft 5148 and have respective camming slots 5512 and 6702 engaged with rollers 5513 and 6704 extending from respective counter register end plates 5514 and 6706. The counter register shaft 313 extends through right and left vertical slots 5515 and 6708 in respective side frames 5507 and 6710 into engagement with respective end plates. Respective studs 5516 and 6712 on the upper portion of each end plate are engaged with corresponding vertical slots 5517 and 6715 in corresponding side frames. As the shaft 5148 is rocked CW, the counter register 211 is cammed to a raised position 211-A for engagement with the single tooth gear 346.

During the first division digitation cycle, the powered sensing slide 5101 (FIG. 51) is driven leftward to the $\div 3$ position in the manner discussed. The lever 5243 (FIG. 52A) is rocked CCW thereby, carrying the stud 5244 to the position $5244 \div 3$. The latch 5246 is rocked CW, unlatching the bail 5250. As during the first digitation cycle of a multiplication operation discussed hereinbefore, rotation of the cam 5216 is suspended at the 180° position by engagement of the pawl tail 5254 with the bail. In addition, the powered sensing slide 5101 is latched in the $\div 3$ position by engagement of the latch 5137 with a notch 5150.

After the digitation portion of the last D_N cycle of a division operation, the accumulator register 207 is in an overdraft condition and the single tooth gear 346 is aligned with the lowest accumulator register order as discussed generally in the "Program Unit" section. Mechanism which is specifically discussed hereinafter is responsive to the overdraft condition of the accumulator register and the single tooth gear being aligned with the lowest order to rock the bail 5250 CCW. Such rocking occurs at the overdraft sensing period (line 39E, FIG. 39) of the cycle following the last D_N cycle, i.e. near the beginning of the last D_R cycle. Thus, during the last D_R cycle, the ratchet gear 5206 engages the pawl 5210 at

180° of the cycle and drives the auxiliary cam line shaft 5203 through the remaining 180° of the cycle. As the shaft 5203 rotates CW, the cam 5216 is carried with the shaft, driving the early slide 5201 leftward. A centralizing surface 5267 is driven against the stud 5265 as the early slide moves leftward, rocking the arm 5147 (FIG. 51), shaft 5148 and box cam 5511 (FIG. 56) CCW. Such rocking cams the end plates 5514 and 6706 and counter register shaft 313 downward, lowering the counter register 211 away from the single tooth gear 346 to the centralized position.

Also during the second 180° of the last D_R cycle, the stud 5141 (FIG. 51) engages the camming surface 5144 and rocks the latch 5137 CCW out of the notch 5150. The powered sensing slide is released thereby for movement rightward by the spring 5110.

Counter register lowered for engagement with racks.—The counter register 211 (FIG. 55) is lowered for engagement with the rack teeth 352 during both the rightward and leftward strokes of the racks of an X_C multiplier entry cycle and a PQ cycle of a division operation, which cycles are discussed hereinbefore in the "Program Unit" section.

During an X_C multiplier entry cycle, the powered sensing slide bail 4519 (FIG. 27) is blocked against the surface 2741-X_C thereby rocking the ear 5105 (FIG. 51) to the position $5105 \div X_C$. With the ear 5105 in this position, a step 5152 is stopped against the ear so that the powered sensing slide 5101 is blocked in a X_C position. During a PQ cycle of a division operation, the powered sensing slide bail 4519 (FIG. 43) is blocked against the surface 4326-PQ, rocking the ear 5105 (FIG. 51) to the position $5105 \div 4$. With the ear in the position $5105 \div 4$, a step 5153 is stopped against the ear so that the powered sensing slide is blocked in a $\div 4$ position. With the powered sensing slide blocked in either the X_C or $\div 4$ positions, a stud 5154 (FIGS. 51 and 52), which is on the slide, is carried to positions $5154 \div X_C$ and $5154 \div 4$ respectively. In either case, the stud cams an early C hook 5268, which is pivoted at 5270 on the early slide 5201, CW against the spring 5263. A hook portion 5271 is raised thereby for engagement with a stud 5273 which is on the lever 5145 (FIG. 51). Thus, as the early slide 5201 is driven rightward during a X_C or $\div 4$ cycle, the arm 5147, shaft 5148 and box cam 5511 (FIG. 55) are rocked CCW, camming the end plates 5514 and 6706 and shaft 313 downward, thereby lowering the counter register 211 into engagement with the rack teeth 352 during the period that the early slide is rightward (line 54B, FIG. 54).

With the powered sensing slide 5101 (FIG. 51) blocked in the X_C or $\div 4$ positions, the stud 5244 (FIG. 52A) is stopped before engagement with the latch 5246. Hence, the bail 5250 remains latched and does not engage the tail 5254, permitting the cam 5216 to return the early slide 5201 leftward during a X_C or $\div 4$ cycle. As the early slide is driven leftward a centralizing surface 5274 is driven against the stud 5273, rocking the lever 5145 CCW and the shaft 5148 and box cam 5511 CW, thereby raising the counter register 211 (FIG. 56) out of engagement with the rack teeth 352.

As discussed hereinbefore in the Nonadd Key portion of the "Control Key Conditioning Mechanism" section, depression of the nonadd key 109 (FIGS. 1 and 6) initiates a multiplier readout cycle during which the counter register 211 (FIGS. 3 and 55) is lowered into engagement with the rack teeth 352 during both the rightward and leftward strokes of the racks so that a multiplier value stored in the counter register is printed and then restored to the register. As discussed, depression of the Nonadd Key with no value in the pin carriage rocks the nonadd bellcrank 4177 (FIG. 41) CCW, driving the ear 4181 (FIGS. 41 and 52) upward. The ear 4181 extends from the early C hook 5268 so that as the bellcrank 4177 is rocked CCW, the hook is raised into engagement with

the stud 5273. During a multiplier readout cycle, therefore, the counter register is first lowered into engagement with the racks and then raised to the centralized position in the same manner as discussed during a $\times_C$ or $\div 4$ cycle.

Late slide

A late slide 5301 (FIG. 53) is provided to bring the multiplier register 209 (FIG. 55) and the counter register 211 into engagement with the rack teeth 352 during $\times_A$ and $\times_{KB}$ multiplier entry cycles. During either of such cycles, the multiplier and counter registers are lowered into engagement with the racks for the leftward stroke of the racks so that the value entered into the racks during the rightward stroke, either from the pin carriage or the accumulator register 207, is transferred to the multiplier and counter registers. During the other multiplier entry cycle, a $\times_C$ cycle which calls for transfer of a stored multiplier value in the counter register 211 to the multiplier register, the late slide forces the multiplier register into engagement with the racks to transfer the value from the racks to the register during the leftward stroke, which value was transferred from the counter register to the racks during the rightward stroke of the racks. Control of the counter register during a $\times_C$ cycle is discussed above in connection with the early slide.

Engaging the multiplier register with the racks during $\times_A$, $\times_C$ and $\times_{KB}$ cycles.—During either a $\times_A$ or $\times_{KB}$ multiplier entry cycle, the powered sensing slide bail 4519 (FIG. 27) is blocked respectively against either the surface 2741- $\times_A$ or the surface 2741- $\times_{KB}$, both of which surfaces are at the level 4519- $\times_A$. In both cases, the ear 5105 (FIG. 51) is carried to the position 5105- $\times_A$ opposite a step 5156 of the powered sensing slide 5101. The powered sensing slide is driven leftward during the cycle to a $\times_A$ position with the step 5156 blocked against the ear 5105. Upon movement of the slide 5101 to the $\times_A$ position, the stud 5127 (FIGS. 51 and 53) is carried to a position 5127- $\times_A$, rocking a late M hook 5303, which is pivoted to the late slide at 5305, CW against a spring 5307. The stud 5127 thereby maintains the hook in engagement with a stud 5308 on the lever 5130 (FIGS. 51 and 53). At the period indicated on line 54C (FIG. 54), a pair of complementary cams 5310 (FIG. 53A) drive a follower 5312, which is keyed to the shaft 5111, CCW. An arm 5313 also keyed to the shaft 5111 is rocked CCW therewith. A stud 5315 on the arm extends into a slot in a bell crank 5316 rocking the bellcrank CW. A stud 5317 extends from the bellcrank into a vertical slot in the late slide 5301, driving the slide rightward as the follower rocks CCW. During such movement, the slide carries the hook 5303 rightward, rocking the stud 5308 and lever 5130 CW, which in turn rocks the shaft 5136 (FIGS. 51 and 55) CCW. The multiplier register 209 is lowered thereby into engagement with the rack teeth 352 after the rightward stroke of the racks 303, line 5A (FIG. 5) and prior to the leftward stroke. After the leftward rack stroke, the late slide is driven leftward, carrying a centralizing surface 5319 against the stud 5308. The lever 5130 is rocked CCW thereby, rocking the shaft 5136 and the box cam 5501 (FIG. 55) CW to raise the multiplier register out of engagement with the teeth 352 to the centralized position.

During a $\times_C$ multiplier entry cycle, the bail 4519 (FIG. 27) is blocked against the surface 2741- $\times_C$ at the level 4519- $\times_C$, thereby rocking the ear 5105 to the position 5105- $\times_C$ opposite the step 5156. With the powered sensing slide 5101 blocked in the $\times_C$ position the stud 5127 is in the position 5127- $\times_C$, holding the hook 5303 in engagement with the stud 5308. The multiplier register therefore is lowered into engagement with the racks and raised therefrom as during a $\times_{KB}$ or $\times_A$ multiplier entry cycle.

Engaging the counter register with the racks for $\times_{KB}$ and $\times_A$ multiplier entry cycles.—During a $\times_{KB}$ or $\times_A$

multiplier entry cycle, the powered sensing slide 5105 (FIG. 51) is blocked in the $\times_A$ position with the stud 5154 in the position 5154- $\times_A$ (FIG. 53). During movement of the stud 5154 to the position 5154- $\times_A$, the stud 5 engages a late C hook 5321 rocking the hook CW into engagement with a stud 5273. The hook 5321 is pivoted to the late slide 5301 at 5322 and is urged CCW by a spring 5323. As the late slide is driven rightward, the stud 5273 is rocked CW, forcing the shaft 5148 (FIGS. 51 and 56) and box cam 5611 CCW so that the counter register 211 is lowered into engagement with the rack teeth 352.

During $\times_{KB}$ and $\times_A$ cycles, the counter register 211 is raised out of engagement with the teeth 352 by engagement of the centralizing surface 5274 (FIG. 52) with the stud 5273 as the early slide 5201 is driven leftward at the period indicated on line 54B (FIG. 54). Thus, during $\times_{KB}$ and $\times_A$ multiplier entry cycles, the counter register is lowered into engagement with the teeth 352 as the late slide is driven rightward and is centralized as the early slide is driven leftward.

PRINTING AND SHORT-CUT CARRY ENABLING MECHANISM

25 A printing and short-cut carry mechanism 5325 (FIG. 53) is provided to sense the position of the powered sensing slide 5101 (FIGS. 51 and 53). According to the position of the slide, the mechanism 5325 enables and disables the printing mechanism 214 (FIG. 2) discussed hereinbefore and a short-cut carry mechanism discussed 30 hereinafter. As discussed hereinbefore in the "Multiplier and Counter Register Controls" section, the powered sensing slide may be blocked in one of seven positions: neutral, $\div 1$, $\times_A$, $\times_C$, $\div 2$, $=2$ and $\div 3$.

Neutral position of the powered sensing slide

The powered sensing slide is blocked in the neutral position, with a step 5138 (FIG. 51) against the ear 5105, during certain cycles that the powered sensing slide bail 4519 (FIG. 45) is held CW by the sensing control plate 4235 (FIG. 45). Such cycles include an add cycle, a minus cycle, a total cycle, a subtotal cycle, and a nonadd cycle. During certain other cycles, the bail 4519 is blocked in the neutral position by a function plate surface which is at the level 4519-N. These cycles include a total or subtotal multiplication cycle, P- cycle, and an RM cycle. 45 During each of the above cycles, a value in the accumulator register is printed. Consequently, the enabling member 3111 (FIG. 31) is rocked CCW to carry the stud 3113 into the notch 3117, as discussed hereinbefore in the "Printing Mechanism, Printing and Paper Advance" section. With the stud 3113 in the notch 3117, printing and paper advance are carried out; and with the stud maintained out of the notch, printing and paper advance are 50 not carried out.

55 During the cycles that the powered sensing slide 5101 is blocked in the neutral position, the stud 3113 is rocked into the notch 3117 by the following means. With the slide 5101 at neutral, the stud 5125 (FIG. 53) is opposite a surface 5327 of a print sensing arm 5329 which is 60 loosely mounted on a shaft 5331. A stud 5333 extends from the arm 5329 into engagement with a slot in a yield link 5334 and is held to the upper edge of the slot by a heavy spring 5336. Every machine cycle, a disk 5338 that is keyed to the main shaft 330 carries a stud 5339 CCW 65 into engagement with a shoulder 5341 of the yield link 5334, forcing the link upward and leftward against a spring 5343. The surface 5327 of the sensing arm 5329 is driven thereby against the stud 5125 on the powered sensing slide, rocking an ear 5344 against an arm of an 70 enabling bail 5346 (FIGS. 53 and 56). The bail is loosely mounted on the shaft 5331 and is rocked CCW by the ear 5344 against a spring 5348 to a print enable position 5346-P (FIG. 56).

75 At the beginning of each cycle, a disk 5601 (FIG. 56), which is keyed to the main shaft 330, carries a stud 5602

out of engagement with a tail 5604 of a delay latch bail 5605, which bail is loosely mounted on a frame shaft 5606. This permits a spring 5608 to rock the bail 5605 CW, driving a delay latch 5609, which latch is pivoted at 5611 to a right arm of the bail 5605, rightward against the bail 5346. When the bail 5346 is raised to the print enable position 5346-P as discussed above, the delay latch 5609 is forced further rightward by the spring 5608 so that a shoulder 5612 underlies the bail, thereby latching the bail 5346 in the position 5346-P.

With the enabling bail 5346 latched in the print enable position 5346-P, a stud 5349 (FIG. 53) which is engaged in a slot 5350 of a print enabling link 5351, is in a raised position. With the stud 5349 raised, the print enabling link 5351 is moved upward by a spring 5353, carrying a stud 5355 to a position 5355-P. The stud 5355 connects the enabling lever 3111 (FIG. 31) to the link 5351 (FIG. 53) so that as the link is moved upward with the bail 5346, the lever 3111 (FIG. 31) is rocked CCW, carrying the stud 3113 into the notch 3117. Since the enabling bail 5346 (FIG. 56) is latched in the print enable position 5346-P the stud 3113 is maintained in the notch 3117 so that the platen 327 is forced thereby against the paper tape and printing segments, as the cams 3127 and 3129 rotate, to print in the manner discussed hereinbefore. The enabling bail 5346 is maintained in the latched position 5346-P until near the end of the cycle when the stud 5602 (FIG. 56) re-engages the tail 5604, forcing the bail 5605 CCW and the delay latch 5609 leftward out of engagement with the enabling bail 5346. This permits the spring 5348 (FIG. 53) to rock the stud 3113 (FIG. 31) out of the notch 3117 and to rock the links 5334 and 5351 (FIG. 53), bail 5346 and arm 5329 to the normal positions shown in FIG. 53.

— 1 position of the powered sensing slide

Movement of the powered sensing slide bail 4519 against the surface 4326—1st— (FIG. 43) during a 1st $\div$ cycle, discussed hereinbefore in the "Program Unit" section, rocks the ear 5105 (FIG. 51) to the position 5105-1 opposite a step 5160 on the powered sensing slide 5101. The slide 5101 is blocked thereby in the $\div 1$ position during a 1st $\div$ cycle so that the stud 5125 (FIG. 53) is in a position opposite a surface 5356 of the print sensing arm 5329. Following such blocking, the stud 5339 is driven against the shoulder 5341, driving the surface 5356 against the stud 5125 which blocks further movement of the arm 5329. This causes the spring 5336 to yield as the link 5334 is driven further upwards by the stud 5339. The bail 5346 (FIGS. 53 and 56) is not driven high enough to overlie the shoulder 5612 by such action so that the delay latch 5609 is blocked against the bail from movement rightward throughout the cycle and does not latch the bail. The stud 3113 (FIG. 31) is maintained thereby out of the notch 3117 so that the platen is not rocked during the cycle and printing thereby prevented. The link 5334 (FIG. 53), the arm 5329, and the bail 5346 are returned therefore by the spring 5348 early in the cycle to the position shown in FIG. 53.

$\times_A$ and $\times_C$ positions of the powered sensing slide

During an $\times_{KB}$, $\times_A$ or $\times_C$ multiplier entry cycle, the powered sensing slide bail 4519 (FIG. 27) is blocked respectively against multiplier plate surfaces 2741- $\times_{KB}$, 2741- $\times_A$ or 2741- $\times_C$ as discussed hereinbefore in the "Program Unit" section. The ear 5105 (FIG. 51) is positioned correspondingly by the bail 4519 in either the position 5105- $\times_C$ during an $\times_C$ cycle or in the position 5105- $\times_A$ during a $\times_{KB}$ or $\times_A$ cycle opposite the steps 5152 or 5156 respectively. During an $\times_{KB}$, $\times_A$ or $\times_C$ multiplier entry cycle therefore, the powered sensing slide 5101 is blocked in either the $\times_A$ or $\times_C$ positions as previously discussed. With the powered sensing slide blocked in either of these positions, a stud 5358 (FIG. 53) on the slide is opposite a surface 5359 of the arm 5329, while the stud

5125 is to the left of the surface 5356. The stud 5339 therefore drives the arm 5329 further CCW than during a neutral cycle to a position in which the surface 5359 is blocked against the stud 5358. The bail 5346 is carried thereby to a short-cut position 5346-SC (FIG. 56) so that as the stud 5602 is carried clear of the tail 5604, the delay latch 5609 is moved fully rightward beneath the bail 5346, latching the bail in the position 5346-SC until the end of the cycle. With the bail 5346 held in this position, the stud 5349 (FIG. 53) rises in the slot 5350, permitting the spring 5353 to raise the link 5351 and rock the stud 3113 (FIG. 31) into the notch 3117 and thereby enable printing in the manner discussed hereinbefore.

Since it is necessary to enter a multiplier value into the multiplier register 209 in short-cut form during a multiplier entry cycle, the bail 5346 is used also to enable a short-cut carry mechanism for such an entry when the bail is in the position 5346-SC by the following means.

A stud 5361 (FIG. 53) which extends from the bail 5346 is blocked in a position 5361-P (FIG. 32) when the bail 5346 is carried to the print position 5346-P (FIG. 56) and is ineffectual in this position to enable a short-cut carry; however, when the bail 5346 is carried to the position 5346-SC (FIG. 56), the stud 5361 is carried to the position 5361-SC (FIG. 32), engaging and driving an enabling hook 3221 to a position 3221-SC against a spring 3223. With the hook 3221 in the position 3221-SC, a hook portion is engaged with a stud 3225 of a cam follower 3227. As the $\times_{KB}$, $\times_A$ or $\times_C$ cycle is carried out, a short-cut carry cam 3229 which is mounted on the main shaft 330 is driven CCW, forcing the follower 3227 CCW and the hook 3221 leftward. The motion of the short-cut carry cam 3229 is indicated on line 54D (FIG. 54). Leftward driving of the hook 3221 rocks a lever 3231 CCW and a shaft 3233 rightward. The shaft is engaged in a slot in the lever 3231 and is urged leftward by a spring 3235. The shaft 3233 extends into guide slots in right and left frame members 3237, only the left being shown in FIG. 32, for horizontal guidance. A sensing hook 3239 is mounted on the shaft 3233 and is forced rightward thereby with the shaft from a normal home position 3233-H to three successive positions: a sensing position 3233-S, a conditioning position 3233-C, and an unlatching position 3233-UL. The sensing hook 3239 is used during entry of short-cut carries into the multiplier register as explained in the following discussion.

Short-cut carry mechanism

When a value is entered into the multiplier register 209 (FIG. 3), during a multiplier entry cycle, whether from the accumulator register 207, the quotient register 211, or the pin carriage, a short-cut carry is registered in a higher order whenever the value in the next lower order is 5 or more. As previously discussed, a multiplier value is entered into the racks 303 either from the pin carriage, the register 207 or the register 211 during the rightward stroke of the racks. During the leftward stroke of the racks, the value is entered into the multiplier register, during which entry, short-cut carries may be registered. Such short-cut carries are accomplished using portions of the tens carry mechanism (FIG. 32) previously described in the Tens Carry Mechanism part of the "Adding Machine Keys and Mechanism" section.

Whether the racks 303 (FIGS. 3 and 32) are stopped by the ejected pins of the pin carriage or the blocked gears of the accumulator register or the quotient register during the rightward stroke, a rack can reach a position representative of 5 at 120° (line 5A, FIG. 5) of a cycle. Also, at 120° (line 54D, FIG. 54) the shaft 3233 is moved by the cam 3229 from the home position 3233-H to the sensing position 3233-S. The sensing hook 3239 associated with each rack is urged CCW by a spring 3245, against a frame shaft 3247 while the shaft 3233 is in the home position. When the shaft 3233 is moved rightward to the sensing position 3233-S, the sensing hooks are car-

ried rightward with the shaft. Any rack 303 which represents a value of 5 is in a position 303-5 and if a rack represents a larger value, the rack is further rightward of the position 303-5.

As the shaft 3233 is moved rightward from the sensing position 3233-S to the conditioning position 3233-C by the cam 3229, each sensing hook which is associated with a rack representing 5 or more is carried horizontally rightward, with the ear 3241 riding along the upper edge of the rack. A hook portion 3249 of each of the hooks associated with an order representing 5 or more overlies or drops on an ear 3251 on the trip slide 3204 associated with the next higher order. The sensing hooks associated with those racks which represent 4 or less rock CCW as the shaft 3233 is moved from the sensing position to the conditioning position so that the hook portions 3249 on these hooks miss the associated ear 3251 and lie beneath the ear 3251.

As the shaft 3233 is moved by the cam 3229 (line 54D, FIG. 54) from the conditioning position 3233-C to the unlatching position 3233-UL, the sensing hooks which have a hook portion 3249 overlying an ear 3251 on the next higher order trip slide 3204 engage the ear and drive the trip slide rightward. The sensing hooks associated with the racks representing 4 or less are rocked clear of the associated ear 3251 and do not disturb the next higher order trip slide. The ear 3206 of each trip slide that is carried rightward is disengaged from the shoulder 3208 of the transfer lever 3210, permitting the transfer lever to rock CW under the urging of the springs 3212 and 354. Such rocking moves the transfer lever ear 3214 clear of the shoulder 3216. Thus, upon return of the racks 303 leftward each rack in an order in which the transfer lever 3210 is rocked is free to move one additional tooth space leftward, thereby registering a short-cut carry from the next lower order.

At the end of the cycle, the bail 3218 is brought upward to engage the transfer lever nose 3220 to restore the transfer lever 3210 to the latched position. Also, at the end of the cycle, the shaft 3233 and sensing hooks 3239 are returned to the home position 3233-H by the cam 3229 (line 54D, FIG. 54).

Powered sensing slide blocked in the $\div 4$ position

During a PQ cycle of a division operation, a quotient value is printed as discussed before in the "Program Unit" section. The bail 4519 (FIG. 43) is blocked against the surface 4326-PQ at the level 4519 $\div 4$ during a PQ cycle. The ear 5105 (FIG. 51) is carried thereby to the position 5105 $\div 4$, opposite the steps 5153 to block the slide in the $\div 4$ position during the cycle.

With the powered sensing slide 5101 (FIGS. 51 and 53) in the $\div 4$ position, the stud 5338 (FIG. 53) is in a position opposite the surface 5327. The print sensing arm 5329 is blocked therefore by the stud 5338 during the cycle, carrying the bail 5346 (FIGS. 53 and 56) to the position 5346-P. This is the same position to which the bail 5346 is raised when the powered sensing slide is in the neutral position. Printing is carried out therefore as discussed before in the "Neutral Position of the Powered Sensing Slide" part of this section.

Powered sensing slide in the $=2$ position

The powered sensing slide 5101 (FIG. 51) is blocked in the $=2$ position with the step 5129 against the ear 5105 during the digitation portion of either a total, subtotal, or negative multiplication operation in the manner discussed hereinbefore in the "Multiplier and Counter Register Controls" section. With the powered sensing slide in the $=2$ position, the stud 5358 (FIG. 53) is opposite the surface 5356 so that the print sensing arm is blocked from CCW rotation, thereby preventing the stud 3113 (FIG. 31) from being lowered into the notch 3117 to enable printing.

Powered sensing slide in the $\div 3$ position

During a $P \div$ cycle of a division operation, digitation is carried out as discussed before in the "Program Unit" section. The powered sensing slide blocked in the $\div 3$ position, as discussed in the "Multiplier and Counter Register Controls" section. With the powered sensing slide in the $\div 3$ position, a stud 5363 (FIG. 53) on the slide is opposite the surface 5356, preventing rotation of the print sensing arm 5329 and movement of the bail 5346 to a print position. The printing mechanism and short-cut carry mechanism therefore remain disabled during division digitation.

COUNTER REGISTER CLEARING MECHANISM

15 A counter register clearing mechanism 5701 (FIG. 57) is provided to clear the counter register 211 (FIG. 55) during 1st $\div$ cycles and X_A and X_{KB} multiplier entry cycles. The counter register is cleared during each 1st $\div$ cycle, prior to the digitation cycles of a division operation, in order that a quotient value may be developed in the counter register during digitation cycles. During multiplier entry cycle, as discussed before, a value is transferred from the racks to the counter and multiplier registers during the leftward stroke of the racks. Consequently, the counter register is cleared prior to the leftward stroke of the racks in preparation for entry of the new multiplier into the counter register.

20 In order to accomplish such clearing, a stud 5162 (FIG. 51A) is mounted on the arm 5124, which arm drives the powered sensing slide 5101. With the powered sensing slide blocked in the $\div 1$ position, the stud 5162 is in a position 5162- $\div 1$; and with the powered sensing slide blocked in the X_A position for a X_A or X_{KB} cycle, the stud 5162 is in a position 5162- X_A . The stud 5162 is pivoted to a link 5703 (FIG. 57), the other end of which link is connected by a stud 5704 to the upper end of an arm 5705 which is mounted on a frame shaft 5707. The stud 5704 extends into a cam slot 5709 of a cam lever 5711 which is pivoted on a frame shaft 5713. 25 A control link 5715 is carried at the upper end of the cam lever at a pivot 5717. A slot in the right end of the control link is engaged with a stationary guide shaft 5719 for movement leftward and rightward. An enabling gear 5721 is mounted on the left end of the control link for simultaneous engagement with a ring gear 5723 (FIGS. 57 and 57A) and a driver gear 5725 when the control link 5715 is moved leftward as indicated in FIG. 57A. When the powered sensing slide 5101 (FIG. 51) is 30 blocked in the $\div 1$ position, the stud 5704 is forced by the stud 5162 to a position 5704- $\div 1$ against a high portion of the cam slot 5709, thereby rocking the cam lever 5711 CCW and carrying the gear 5721 into engagement with the gears 5723 and 5725. In a similar manner, the stud 5704 is driven to a position 5704- X_A against the high portion of the slot 5709 when the powered sensing slide is driven to the X_A position, thereby rocking the cam lever 5711 CCW and engaging the gear 5721 with gears 5723 and 5725. When the powered sensing slide is in any other position, the cam lever 5711 is maintained substantially in the position shown with the stud 5704 against a lower portion of the slot 5709 so that the gear 5721 is clear of the gears 5723 and 5725.

35 In order to drive the driver gear 5725 for clearance of the counter register, an intermittent driving gear 5727 and a locking disk 5729 are provided, both are keyed to the main shaft 330. Counterclockwise rotation of the shaft 330 brings a stud 5731 mounted on the disk 5729 into engagement with an upper edge of a slide 5733 which is mounted for sliding movement on a guide shaft 5735 and the guide shaft 5719. The slide normally is held upward in the position shown by a spring 5737. Engagement by the stud 5731 with the upper edge of the slide forces the slide downward, carrying an ear 5739 into a notch 40 5741 if the cam lever 5711 is rocked CCW or into a notch 45 5741 if the cam lever 5711 is rocked CCW or into a notch 50 5741 if the cam lever 5711 is rocked CCW or into a notch 55 5741 if the cam lever 5711 is rocked CCW or into a notch 60 5741 if the cam lever 5711 is rocked CCW or into a notch 65 5741 if the cam lever 5711 is rocked CCW or into a notch 70 5741 if the cam lever 5711 is rocked CCW or into a notch 75 5741 if the cam lever 5711 is rocked CCW or into a notch

5743 if the lever is not rocked. The cam lever is locked thereby so that the gear 5721 is locked either in or out of engagement with the ring and driver gears. Later on in the cycle, a second stud 5745 mounted on the disk 5729 engages the upper edge end of the slide 5733 to maintain the ear 5739 in engagement with one of the notches 5741 or 5743 after the stud 5731 moves away from the slide. Immediately following locking of the enabling gear 5721 with the ring and driver gears, teeth 5747 on the intermittent driving gear engage a gear 5749 and rotate the gear one complete revolution from 35° to 155° of every machine cycle as indicated on line 54E (FIG. 54). The gear 5749 is engaged with an idler gear 5751 which is engaged with the ring gear 5723 (FIG. 57A). The ratio of teeth between the intermittent driving gear 5727, the gear 5749, the idler gear 5751 and the ring gear 5723 is such that the ring gear is driven one full revolution whenever the teeth 5747 engage and drive the gear 5749. The gear 5725 (FIG. 57A) is connected to the gear 5723 through the gear 5721. The gear 5725 is integral with a key way 5753 on the end of a shaft 5755. The gear 5723 is loosely mounted on the shaft 5755 so that during cycles that the gear 5721 is not leftward, the ring gear is idly rotated. The keyway 5753 is engaged with a key 5757 (FIG. 57A) formed on the left end of the counter register shaft 313 (FIGS. 55 and 57B). Counter register numeral wheels 309 are ordinarily arranged on the shaft 313 to freely rotate. Each wheel 309 is provided with a lug 5759 (FIGS. 55 and 57A) projecting from the side of one tooth. A comb 5761 is fitted in a slot in the counter register shaft 313 with teeth 5762 that extent outwardly for engagement with respective lugs 5759. Each numeral wheel 309 of the counter register is provided with 12 teeth and may be at a position representing a value from 0 to 10. In any position from 0-9, the wheel may represent a quotient or multiplier value and is driven to position 10 during a division digitation cycle which causes an overdraft. Whenever clearance of the counter register is initiated in the manner discussed, the keyway 5753 (FIG. 57A) and comb 5761 are rotated one complete revolution CW (FIG. 55). The teeth of the comb are driven thereby against respective lugs 5759, driving the lugs and the numeral wheels to the zero position shown in FIG. 55, thereby clearing the register.

Since the gear 5725 is driven precisely one complete revolution during each clearance operation, the keyway 5725 and the key 5757 are invariably aligned vertically at the end of the operation. With the keyway and the key so aligned the counter register shaft 313 may be vertically moved either downwardly to bring the numeral wheels into engagement with the racks or upwardly for engagement with the single tooth gear 436. During either of these periods, the numeral wheels may be rotated independently of the counter register shaft 313. The driver gear 5725, keyway 5753, key 5757, and shaft 313, however, remain vertically aligned during these periods in order to facilitate raising and lowering of the counter register and to provide an index position for readout and clearance of the register. Such alignment is achieved by means of a centralizer 5763 which remains normally engaged with the gear 5725 except during clearance. The centralizer is pivoted to and carried by the cam lever 5711 and is guided by a stud 5765 extending from the centralizer into a vertical slot in the frame 5507. When the cam lever 5711 is rocked CCW for a counter register clearance, then the centralizer is lowered out of engagement with the driver gear 5753.

In order to maintain the counter register numeral wheels 309 (FIG. 55) in the zeroized position in which they are shown in FIG. 55 after a counter register clearance operation, a detent 5519 is provided for each wheel. The detents also maintain the numeral wheels 309 in whichever position that they are driven by the single tooth gear 346 when the counter register is raised for engage-

ment with the single tooth gear during a division operation. When the counter register is lowered for engagement with the rack teeth 352, the detent 5519 is rocked out of engagement with the wheel 309 to permit free rotation of the wheels by the racks. The detents 5519 are mounted on a shaft 5516 which is carried in right and left end plates 6706 and 5514. Each detent is also mounted in a frame 5520 which is carried by the shaft 5516 and which parallels the register. An ear 5521 on each end of the frame 5520 has a stud 5522 which extends into guide slots 5523 in right and left side frames 6710 and 5507. Each detent 5519 is spring urged into engagement with a respective numeral wheel by a spring 5524 between the detent and the frame. As long as the end plates maintain the counter register in the centralized position shown or in a raised position for engagement with the single tooth gear, the detents are maintained against respective numeral wheels by the guide slot 5523. When the register is lowered into engagement with the rack teeth 352, however, the lower end of the guide slot, which extends slightly rightward, permits the stud 5522 to move rightward when the numeral wheels are rotated, thereby rocking the detents away from the numeral wheels. Whenever the register is raised from the rack teeth 352, the stud 5522 is cammed leftward re-engaging the detents with respective numeral wheels. Such an arrangement relieves the load on the rack drive.

In order to maintain the gear 5749 (FIG. 57) in a position for engagement with the teeth 5747 on the driving gear 5727, and in order to maintain the ring gear 5723 in a position for engagement with the enabling gear 5721, a locking plate 5767 is formed on the gear 5749 and is provided for engagement with the disk 5729. The relationship of the disk 5729 and the locking plate 5767 is such that when a space 5769 which is formed in the disk 5729, moves adjacent a tooth 5771 on the locking plate, the teeth 5747 are ready for engagement with the gear 5749. The space 5769 permits the locking plate 5767 to rotate with the gear 5749. A second space 5773 is provided in the disk for engagement with a second tooth 5774 on the locking plate to permit the locking plate to rotate with the gear 5749 back into the locking position with the disk as the teeth 5747 rotate out of engagement with the gear 5749. The gears 5749 and 5723 are thereby maintained locked in aligned positions after the clearance period.

SINGLE TOOTH GEAR DRIVING MECHANISM

The single tooth gear 346 (FIG. 3), which is used for counting the multiplier register 207 to zero during a multiplication operation and for developing a quotient in the counter register 209 during a division operation, is mounted for lateral movement on a shaft 381 (FIGS. 59A and 60). As best shown in FIGS. 55A and 60, the single tooth gear 346 is mounted on the shaft 381 between the sides of a countout carriage 6001 and has teeth 5901 extending into keyways 5903 which run the length of the shaft. The framework 6001 is slideably mounted on shafts 381 and 6003 for lateral movement. The single tooth gear, therefore, may be rotated with the shaft 381 as well as moved laterally along the shaft with the countout carriage. Normally, the countout carriage is latched in the position shown, aligned with the 5th order rack assembly 300-5 by means of bail 6005 which is mounted on the shaft 6003 and which straddles the sides of the countout carriage. The bail 6005 has a key 5539 extending into a keyway 5540 which runs the length of the shaft, permitting the bail to move freely with the countout carriage as well as to be driven by the shaft as presently described. Normally, the bail is held by the shaft in the position shown in FIG. 55 so that a nose 5541 on the bail is engaged with a tab 5542 extending downward from a crossframe member 5543 (FIGS. 55A and 60). The countout carriage 6001 is held rightward

thereby in the position shown against the urging of a spring 6007.

During a $P=$ cycle of a multiplication operation or during a $P \div$ cycle of a division operation, both of which cycles are discussed generally hereinbefore in the "Program Unit" section, the shaft 6003 is rocked CCW by means specifically discussed hereinafter in a "Lineup Mechanism" section. When the shaft is rocked CCW, the bail 6005 is carried CCW therewith, driving at least one of a pair of bail teeth 6009 and 6010 into engagement with teeth 6012 (FIG. 60A) of a locking comb 6013 which extends from the pin carriage 205 (FIGS. 3 and 23A). The countout carriage and pin carriage are latched together thereby, and the nose 5541 is rocked clear of the tab 5542. The nine pin stop 1901 (FIG. 19) is driven CCW away from the nine pins 304-9 by means discussed hereinafter to permit the carriages to escape leftward to a lineup position, the means for blocking in the lineup position also being discussed hereinafter. After such latching and escapement leftward for lineup, the single tooth gear 346 is driven either CW for multiplier values that are not shortcut (D_N cycles) or CCW for values that are shortcut (D_R cycles) during multiplication and CCW for D_N cycles and CW for D_R cycles during division digitation cycles. Mechanism for so driving the single tooth gear during digitation cycles and for maintaining the single tooth gear in neutral at other times is shown in FIGS. 59 and 59A.

Control of the rotation of the single tooth gear 346 is by means of the program unit 229. Specifically, the single tooth gear 346 is controlled by the single tooth gear bail 4521 (FIG. 45). As discussed hereinbefore in the "Program Unit" section, the single tooth gear bail 4521 is urged CCW against the sensing control plate 4235 so that as the plate is moved leftward the bail is rocked CCW against the surface of an active function plate opposite the bail, which surface is at one of the levels 4521 N, CCW, CW or LU. As the bail 4521 is rocked COW, a nose 4552 of a lever 4554 which is engaged with an arm of the bail 4521 is permitted to rock leftward in FIG. 45 and CCW in FIG. 59 as the bail 4521 is rocked CCW. A right side view of the bail 4521 along with the lever 4554 is shown in FIG. 59. As the bail 4521 is rocked CCW, the lever 4554 is urged CCW by a spring 5905. The lever 4554 is keyed to a shaft 5907 which is rocked COW with the lever. A swash cam 5909 also is keyed to the shaft 5907 and is rocked CCW therewith. The upper edge of the swash cam is bent at angles best shown in FIG. 59A which is an enlarged view of FIG. 59 taken generally along lines 59A-59A. The angled edge of the cam is engaged in a slot 5911 in a stub shaft 5913. The shaft 5913 is mounted internally in a hole 5915 which is drilled in the left end of the shaft 381.

As the swash cam 5909 is rocked CCW when the bail 4521 is rocked, the shaft 5913 is cammed rightward into the hole 5915. A center portion 5917 of the shaft 5913 is reduced, leaving space for mounting a sliding key 5919. The ends of the key extend into slots 5921 formed in the left end of the shaft 5913, which end is shown cut away in FIG. 59A along the slots. Such an arrangement permits the sliding key 5919 to rotate about the shaft 5913 even though the shaft remains stationary; but at the same time the sliding key may be moved laterally in the slots 5921 and rotate with the shaft 381. A pair of gears 5923 and 5924 are mounted freely on the end of the shaft 381 for rotation in opposite directions by means presently described. Slots 5926 and 5927 are formed in internal portions of the gears 5923 and 5924 respectively. These slots are for engagement with ends 5929 and 5931 respectively of the sliding key.

As long as the single tooth gear bail 4521 remains in the position shown in FIG. 45 or is rocked to the position 4521-N, a portion 5909-N (FIG. 59A) of the swash cam 5909 remains in the slot 5911 of the shaft 5913 so

that the sliding key 5919 remains in the position shown. Rotation of the gears 5923 and 5924 with the key in this position cannot rotate the shaft 381.

When the bail 4521 is rocked to the position 4521-CCW, a surface 5909-CCW is in the slot 5911. Movement of the swash cam to this position cams the shaft 5913 and the sliding key 5919 rightward so that ends 5931 engage the gear 5924 in slots 5927. Such engagement permits the gear 5924 to drive the shaft 381 CCW.

Further CCW rocking of the single tooth gear bail 4521 to either the position 4521-CW or the position 4521-LU moves the swash cam to positions in which the surface 5909-CW or 5909-LU respectively is in the slot 5911. In either case, the sliding key 5919 is moved further rightward to a position in which the ends 5929 engage slots 5926 in the gear 5923, leaving the other ends 5931 clear of the slots 5927. This engagement permits the gear 5923 to drive the shaft 381 CW.

The drive for the gears 5923 and 5924 is by means of the gear 5727 (FIG. 57) discussed hereinbefore in the "Counter Register Clearing Mechanism" section. As discussed in that section, the gear 5727 is driven one complete revolution every machine cycle during the period indicated on line 54E (FIG. 54). The gear 5749 is keyed to the shaft 5735 for rotation therewith. A gear 5933 (FIG. 59) also is keyed to the shaft 5735 for rotation therewith. The gear 5933 is driven therefore one complete revolution during the period indicated on line 54E. A gear train comprising gears 5935, 5936 and 5937 enables the gear 5933 to drive the gear 5924 CCW and the gear 5923 CW according to the setting of the program unit. The shaft 381 and single tooth gear 346 are driven therefore one complete revolution CCW or CW during those cycles in which the sliding key 5919 is engaged with either the gear 5923 or the gear 5924. The single tooth gear thereby drives the controlling numeral wheel 307 of the multiplier register during multiplication or the active numeral wheel 309 of the counter register during division one tooth space CW or CCW as called for by the program unit. Such driving is carried out during the period indicated on line 54E.

LINEUP MECHANISM

A lineup stop 5526 (FIG. 55A) is associated with each assembly 300. During either an $\times_{KB}$, $\times_A$ or $\times_C$ multiplier entry cycle, the stop 5526 to the left of the highest multiplier order is rocked to a position 5526-M for blocking the pin carriage 205 and the countout carriage 6001. The carriages are escaped leftward against the rocked stop during a $P=$ cycle so that the single tooth gear 346 and the lowest order multiplicand value in the pin carriage are aligned with the highest order of the multiplier value. During a 1st- $\div$ cycle of a division operation the lineup stop to the left of the highest dividend order is rocked to a position 5526-D for blocking the pin carriage and countout carriage. During the next cycle of a division operation (a $P \div$ cycle), the carriages are escaped leftward against the rocked stop so that the highest order divisor value is aligned with the highest order dividend value.

The lineup stops 5526 are mounted on a shaft 5527 which has two lateral grooves formed along the length of the shaft, a CW groove 5528 and a CCW groove 5529. A "C" spring 5530 is mounted on a hub 5531 that is part of each lineup stop, with one end of the spring rounded or bent over extending through a hole 5532 in the hub into normal engagement with the CW groove 5528. The spring 5530 is engaged normally with the groove 5528 and holds the lineup stop in a nonblocking position clear of the pin carriage and countout carriage. When the spring is detented to the CCW groove 5529, as presently discussed, the lineup stop is held either in the position 5526-M for blocking the pin carriage and countout carriage for multiplication lineup or in the position 5526-D for division lineup.

During any multiplier entry cycle (X_{KB} , X_A or X_C), the lineup stops 5526 associated with the orders to the left of the highest order of the multiplier value are detented CCW so that the spring 5530 is in the CCW groove 5529. Near the end of a multiplier entry cycle, the shaft 5527 is rocked to bring the lineup stops, which are to the left of the highest multiplier order, to the position 5526-M.

Lineup stops set during multiplier entry cycle.—Depression of the multiplier entry key 110 releases the multiplier plate 2714 (FIG. 27) to move to one of three positions in the manner discussed hereinbefore in the "Program Unit" section. A multiplier entry cycle is initiated thereby during which the multiplier register 209 (FIG. 55) is carried downward by the end plate 5504 into engagement with the rack teeth 352. An ear 5802 (FIGS. 55, 58 and 58A) on the end plate 5504 overlies a lineup setting link 5803. When the plate 5504 is lowered, the ear 5802 forces the link 5803 CCW about a stud pivot 5804, bringing a hook portion 5805 to a position 5805-A so that a surface 5810 is in the path of an ear 5806 on a lineup setting and resetting rack 5807. The link 5803 is driven CCW by the ear 5802 against a spring 5819 which is between the link 5803 and a lineup reset link 5820 which is also pivoted at 5804. The reset link 5820 is prevented from CCW rotation by engagement with the bottom of a slot in a frame member 5821. The rack 5807 is engaged with a lineup setting and resetting gear segment 5808 which is keyed to one end of the shaft 5527 (FIGS. 55 and 58) for rocking and positioning the lineup stops 5526.

The shaft 5527 is driven CW from a centralized position 5808-C to a lineup stop setting position 5808-S by the cam 3229 which is mounted on the main shaft 330. As the cam 3229 is rotated CCW, a stud 5809 is carried to a position 5809-A against a drive lever 5812. The stud 5809 drives the lever 5812 CW about a shaft 5813 against the urging of a spring 5814 which is connected between a pair of centralizer levers 5815 and 5816. The levers are mutually urged by the spring 5814 against a frame stud 5817 and a stud 5818 on the lever 5812. As the lever 5812 is driven CW by the stud 5809, the link 5803, which is pivoted to the lever 5812 at 5804, is driven leftward, forcing a surface 5810 against the ear 5806. The rack 5807 is driven leftward thereby, rocking the gear segment 5808 to the position 5808-S. Such leftward driving is against a centralizing spring 5823. Normally, the rack 5807 is held centralized by means of a centralizing lever 5824 which is held CW against a frame stud 5825 by the spring 5823. The rack 5807 is urged leftward to the centralized position by a spring 5827 holding a stud 5826 on the rack against the lever 5824.

During a multiplier entry cycle the rack assemblies 300 (FIG. 3) are urged rightward. The main members 301 all move rightward to at least the zero position. The members 301 which are to the left of the highest order digit are restored to the subzero position shown in FIGS. 3 and 55 by the zero suppression mechanism discussed before in the "Adding Machine Keys and Mechanism" section. With a member 301 in the subzero position, a subzero ear 5534 formed on the member 301 underlies a nose 5535 (FIG. 55A) of the associated lineup stop 5526. The CW rocking of the shaft 5527 (FIG. 58) and the lineup stops 5526 (FIG. 55) by the rack 5807 discussed above occurs during the rightward stroke of the assemblies 300 (FIG. 3). Consequently, in value representing orders, the subzero ear 5534 is rightward, clear of the nose 5535 during the rocking. In these orders, therefore, the lineup stops 5526 are rocked CW with the shaft 5527 and remain in the same relative positions with respect to the shaft with the spring 5530 in the groove 5528. In the orders to the left of the multiplier value, the members 301 are restored to the subzero position with the subzero

ear 5534 beneath the nose 5535. In each of these orders, the lineup stop is blocked by the ear 5534 from CW rotation with the shaft 5527 so that as the shaft is rocked CW, the spring 5530 is detented from the CW groove 5528 to the CCW groove 5529.

As the cycle continues, the stud 5809 is rotated to a position 5809-B to the right of the shoulder 5811. This permits the spring 5814 to rock the lever 5812 CCW and the link 5803 to centralized positions freeing the rack 5807 for movement rightward to the centralized position under urging of the spring 5823. The gear segment 5808 and shaft 5527 are driven CCW thereby to the centralized position 5808-C. All of the lineup stops 5526 (FIG. 55) are rocked CCW with the shaft 5527. Those stops which were not detented from the CW groove 5528, i.e. those which are associated with orders of the multiplier value, are returned to the normal position shown. Those stops which lie to the left of the multiplier value and were detented to the CCW groove 5529 are returned to the position 5526-M.

As the cam 3229 continues to rotate, the stud 5809 is carried to a position 5809-C for engagement with a hook 5828 on the right end of the lever 5812. Such engagement forces the lever 5812 CCW against the spring 5814, driving the hook portion 5805 of the link 5803 rightward against the ear 5806 on the rack 5807. This forces the ear 5806 to a backset position 5806-BS and the rack 5807 rightward to a corresponding position. The gear segment 5808 and the shaft 5527 are rocked CCW thereby to a backset position 5808-BS. The lineup stops which have springs 5530 in the CCW groove 5529 are rocked CCW therewith, normally carrying a tail 5537 to a position 5537-A. The tail 5537 of the lineup stops with springs in the CW groove 5528 are carried to a position 5537-B. Just prior to such rocking, i.e. between the time that the stud 5809 rotates from position 5809-B to position 5809-C and engages the hook 5828, the members 301 are returned leftward to the subzero position. If the highest order multiplier value is 5 or more, the rack 303 to the left of that value is moved one tooth space leftward at this time to register a short-cut carry in the manner discussed hereinbefore in the "Printing and Short-cut Carry Enabling Mechanism" section. As the rack 303 is moved leftward to register the short-cut carry, a short-cut carry ear 5538 (FIG. 55A) is moved to a position 5538-A. As a result, CCW rocking of the shaft 5527 to the position 5527-BS and the higher order stops 5526 to the position 5537-A forces the tail 5537 of the stop in the order in which the highest order short-cut carry is registered against the corresponding short-cut carry ear 5538. The spring 5530 in this stop is detented thereby from the CCW groove 5529 to the CW groove 5528.

As the cam continues to rotate, the stud 5809 is carried to a position 5809-D out of engagement with the hook 5828, permitting the spring 5814 to centralize the lever 5812 as well as the link 5803. The rack 5807 is freed thereby for centralization by the spring 5827. As the rack is centralized leftward, the shaft 5527 and gear segment 5808 are rocked CW to the centralized position 5808-C. All of the stops with springs 5528 in the CW groove, i.e. the stops in the orders of the multiplier value, are rocked to the normal position shown in FIG. 55A. All of the stops with springs 5528 in the CCW groove, i.e. the stops to the left of the multiplier value, are rocked to the position 5528-M into the path of a tab 5544 on the countout carriage for blocking the carriages in a lined-up position during a P= cycle in the following manner.

Countout carriage and pin carriage latched together, then released leftward for lineup during P= cycle.—After entry of a multiplicand into the pin carriage, either the total = key 112 (FIG. 1), the subtotal = key 114 or the negative = key 116 is depressed to initiate multiplication. Such depression releases the total plate 4231 (FIG. 47) to the P= position or the negative plate 4233 (FIG.

48) to the $P=$ position. A $P=$ or $P=-$ cycle is initiated and carried out thereby in the manner discussed hereinbefore in the "Program Unit" section. As discussed in that section the sensing control plate 4235 (FIG. 45) is released leftward, permitting respective sensing elements 4515, 4517, 4519 and 4521 to move against opposite surfaces on the active function plate. During any of the multiplication cycles ($T=$, $ST=$, $-T=$, or $-ST=$) either the surface 4724P= (FIG. 47) of the total plate or the surface 4824P= (FIG. 48) is opposite the single tooth gear bail 4521 to block the bail at the level 4521-LU. When the bail 4521 is rocked CCW to the level 4521-LU, the swash cam 5909 (FIG. 59) is rocked CCW therewith as discussed hereinbefore in the "Single Tooth Gear Driving Mechanism" section. With the bail 4521 against a $P=$ or $P=-$ surface, the swash cam 5909 is rocked CCW to a position in which a nose 5939 (FIGS. 59 and 61) is in a position 5939-A. In rocking to this position, the nose 5939 is driven against a stud 6101 extending from an interponent 6103. The interponent is pivoted at 6105 on a latching arm 6107 and is normally held in the position shown by a spring 6109 between the interponent and the latching arm. The spring 6109 holds an ear 6111 of the interponent against a shoulder of the latching arm. This arrangement permits the nose 5939 to rock the interponent CW until the nose is clear of the stud 6101 and then the spring 6109 returns the interponent to the normal position.

During a $P=$ or $P=-$ cycle, after the racks are driven rightward to drive the printing segments to positions for printing the multiplicand, in the manner discussed hereinbefore and as indicated on line 5A (FIG. 5), the sensing control plate 4235 (FIG. 45) is driven rightward during the period indicated on line 39C (FIG. 39). As the sensing control plate is driven rightward, the bail 4521 is cammed CW, forcing the swash cam 5909 (FIGS. 59 and 61) CW therewith. During such rocking the nose 5939 engages the stud 6101 driving the interponent 6103 and the latching arm 6107 CCW about a shaft 6115 against a spring 6117. This movement releases an ear 6119 from engagement with a shoulder 6121, releasing a member 6123 from which the ear extends for CCW rocking by a spring 6125. The member 6123 is keyed to the shaft 6003 (FIGS. 55A, 60 and 61), which shaft is rocked CCW with the member. As the member 6123 is rocked CCW, the ear 6119 rides CCW along a surface 6127, holding the latching arm 6107 CCW against the spring 6117. Later in the multiplication operation, the latching arm 6107 and member 6123 are restored in a manner discussed hereinafter.

Clockwise rocking of the member 6123 and the shaft 6003 forces the bail 6005 (FIG. 55A), which is also keyed to the shaft 6003, CCW, driving either one or both of the bail teeth 6009 (FIG. 60) and/or 6010 into engagement with the locking comb teeth 6012. Since the locking comb 6013 is fastened to the pin carriage 205, such engagement latches the countout carriage 6001 to the pin carriage. Counterclockwise rocking of the shaft 6003 and bail 6005 by the member 6123 also moves the nose 5541 clear of the tab 5542, thereby freeing the countout carriage for movement leftward. Counterclockwise rocking of the member 6123 also drives a nose 6129 against an arm 6131 (FIGS. 19 and 61) of the nine pin stop 1901. The nine pin stop 1901 is driven CCW thereby clear of the row of nine pins 304-9. Normally, the nine pin stop 1901 restrains leftward movement of the pin carriage under urging of the spring 2612 (FIG. 26) by engagement of the stop with a nine pin.

Such CCW rocking of the member 6123 thereby latches the countout carriage to the pin carriage and frees the carriages for movement leftward under urging of the spring 6007 (FIG. 60) and the spring 2612. The carriages move leftward until the tab 5544 (FIGS. 55A and 60) which tab extends from the left side of the countout carriage 6001, is stopped against the lineup stop

5526 which is to the left of the highest multiplier order. This stop is in the position 5526-M to which it was set during the multiplier entry cycle which preceded the multiplication operation, as discussed hereinbefore.

5 Thus, at the end of a $P=$ cycle, the pin carriage and countout carriages are positioned so that the single tooth gear 346 and the lowest multiplicand order are aligned with the highest multiplier order.

Countout carriage held by holding rack, then lineup stops reset during first digitization cycle.—As discussed hereinbefore in the "Program Unit" and "Multiplier and Counter Register Controls" sections, the multiplier register 209 (FIG. 55) is raised for engagement with the single tooth gear 346 at the period indicated on line 54B (FIG. 54) of the first digitization cycle of a multiplication operation. As discussed therein, the box cam 5501 (FIG. 55) is rocked CW to raise the multiplier register. Such movement releases a holding rack 5545 (FIGS. 55A and 60) to rock CW to a position 5545-A by means presently described. This brings the rack into engagement with a nose 5446 which extends from the left side of the countout carriage 6001. The countout carriage and pin carriage are held thereby in the aligned position by the holding rack.

25 When the box cam 5501 is rocked CW, a stud 5547 (FIGS. 55 and 62) that extends from the cam, is driven against a digitization lever 6201, rocking the lever CCW about a shaft 6203. Such rocking drives a nose 6205 against an ear 6207 on a latch lever 6209, thereby rocking the latch lever CW against a spring 6211. The lever 6209 is rocked thereby out of engagement with a stud 6213 on a latch 6215. On the lower end of the latch 6215 a nose 6217 is normally engaged with a stud 6219 extending from a right arm 6221 (FIG. 62B) of a shift rack 6223. This permits a spring 6225 to rock the shifting rack CW to the position 6223-A (FIG. 55A). A nose 6227 (FIGS. 62 and 62B) is formed on a right arm 6229 of the holding rack 5545 for engagement with the lower edge of the shifting rack 6223. As the shifting rack is rocked CW, a spring 6231 moves the holding rack CW, with the nose 6227 against the shifting rack. When the multiplier register is raised for engagement with the single tooth gear 346 at the beginning of a first digitization cycle of a multiplication operation, the holding rack 5545 and shifting rack 6223 are rocked thereby into engagement with the countout carriage nose 5546 to hold the countout carriage and the pin carriage in aligned positions with the multiplier register. The carriages are held by the holding rack and shifted rightward by the shifting rack at periods and by means discussed in other sections hereinafter.

50 With the carriages held aligned by the holding rack, the lineup stops 5526 (FIG. 55) are reset to the original position with all of the springs 5530 in the CW groove 5528 and the shaft 5527 rocked to the position shown.

55 When the multiplier register shaft 312 is raised by the early slide 5216 (FIG. 52), near the beginning of the first digitization cycle (line 54B, FIG. 54), to the centralized position for engagement with the single tooth gear, in the manner discussed hereinbefore, the multiplier register end plate

60 5504 is raised with the shaft 312. The ear 5802 (FIGS. 55 and 58) is removed thereby from engagement with the lineup setting link 5803 to permit the spring 5819 to rock the link 5803 CW, clear of the ear 5806 on the rack 5807. Raising of the multiplier register end plate 5504 also forces the ear 5802 against a reset pickup lever 5831 (FIG. 58) which lever is pivoted at 5832 on the lineup reset link 5820 and is spring urged CCW by a spring 5833 between the link 5820 and the lever 5831. As the ear 5802 forces the lever 5831 upwards, the link 5820 is carried

70 CW about the stud 5804 to a position of engagement with the ear 5806 on the rack 5807. Next, the stud 5809 on the cam 3229 is driven against the lever 5812, driving the lever leftward. Since the link 5820 is carried by the stud 5804 in a slot 5834, the stud is driven leftward, free of

the link 5820. The link 5820 is prevented from drifting leftward by a stud 5835 which extends from the link into engagement with the frame member 5821 which also guides the link. The rack 5807, segment 5808, and lineup stops 5526 therefore remain stationary when the link 5812 is rocked CW.

When the stud 5809 is rotated to the position 5809-C, the stud 5804 is in the right end of the slot 5834. When the drive lever 5812 is driven CCW by the stud 5809, a hook portion 5837 in the link 5820 engages and drives the ear 5806 rightward to a reset position 5806-R. The rack 5807 is driven rightward thereby, rocking the segment 5808 and shaft 5527 CCW to a reset position 5808-R. This rocking carries each of the lineup stops 5526 (FIG. 55A) to a position 5526-R, into engagement with the bottom of a tooth space 5548 of a guide comb 5549 which guide the lineup stops. This engagement forces all of the stops which have springs 5530 in the CCW groove 5529 to detent to the CW groove 5528.

Upon disengagement of the stud 5809 with the hook 5828, the drive lever 5812 is rocked CW to the centralized position by the spring 5814. This action permits the rack 5807 to return leftward to the centralized position under the urging of the spring 5827.

When the lineup reset link 5820 is carried rightward to drive the ear 5806 to the position 5806-R, the reset pickup lever 5831 is also carried rightward and out of engagement with the ear 5802. The lever 5831 is rocked CCW thereby by the spring 5833 to a position in which a stud 5838 is against the lower edge of the link 5820. When the link 5820 and the lever 5831 are returned to the centralized positions, the left edge of the lever 5831 is against the right edge of the ear 5802 which is still raised, to permit the spring 5819 to rock the links 5831 and 5820 CCW to the positions shown. During the period that the links 5820 and 5831 are rightward, the link 5820 is held engaged with the ear 5806 by a beveled edge of the surface 5837 so that the link 5820 is not rocked out of engagement with the ear 5806 until the surface is clear of the ear when the link 5820 and the rack 5807 are centralized. Centralization of the rack 5807 rocks the segment 5808, the shaft 5527 and all of the stops 5526 CW to the normal position shown in FIG. 55. The lineup stops 5526 are not rocked during subsequent digitation cycles since the lineup reset link 5820 and lineup setting link 5803 are clear of the ear 5806 when the drive lever 5812 is rocked by the cam 3229.

Thus, during the first digitation cycle, the countout carriage 6001 is held by the holding rack 5545 and the lineup stops 5526 are reset and rocked to normal positions.

Division lineup

Prior to initiation of a division operation, a dividend is entered into the accumulator register 207 (FIGS. 2 and 3) by means of the add-total key 103 (FIG. 1) or is in the accumulator register as a result of a prior operation. Next, a divisor is entered into the pin carriage by means of value keys 101. Finally, a division operation is initiated by depression of the divide = key 118. The first cycle of a division operation is a 1st ÷ cycle, as discussed hereinbefore, during which cycle the shaft 5527 (FIG. 55A) is rocked CW to carry lineup stops 5526 to the left of the highest order of the dividend value against respective subzero ears 5534, detenting those stops from the CW groove 5528 to the CCW groove 5529. The shaft 5527 is then centralized, returning the detented stops to a position 5526-D in the path of a tab 5550 extending from the left edge of the pin carriage locking comb 6013. The non-detented stops are carried to a position 5526-K, clear of the tabs 5550 and 5544. The next cycle is a P÷ cycle during which the countout carriage 6001 and pin carriage 205 are latched together with the single tooth gear 346 aligned with the lowest divisor order. The carriages are then released to escape leftward until the tab 5550 is blocked against the lineup stop to the left of the highest

order of the dividend value. With the carriages so blocked, the highest divisor order is aligned with the highest dividend order. The next cycle is a first digitation cycle during which the holding rack 5545 is raised into engagement with the countout carriage to maintain the pin carriage and countout carriage in the aligned position. After such engagement, the shaft 5527 is rocked CCW forcing the lineup stops against the bottom of the tooth spaces of the comb 5549, thereby resetting all of the springs 5530 which are in the CCW grooves 5529 to the CW groove 5528.

1st ÷ cycle.—Depression of the divide = key 118 releases the division plate 4301 (FIG. 43) for movement leftward to the 1st ÷ position. With the division plate in this position, a counter register clearance is carried out in the manner discussed hereinbefore in the "Counter Register Clearing Mechanism" section. During such clearance, the counter register shaft 313 (FIG. 55) is driven one revolution in the CW direction. A division lineup conditioning disk 5840 (FIG. 58A) is keyed to the right end of the counter register shaft 313 so that upon CW rotation of the shaft, a nose 5841 on the disk is driven against an ear 5842 on a conditioning slide 5843. The slide 5843 has slots which are mounted for vertical movement in grooves of frame shafts 5844 and 5845. A latch 5846 is pivoted at 5847 to the slide 5843 and is urged CCW against the stud 5845 by a spring 5848 between the latch and slide. The slide 5843 is driven downward by the nose 5841 as the disk 5840 is driven CW. The latch 5846 is carried downward therewith to a position to permit the latch to rock CCW beneath the stud 5845, thereby latching the slide 5843 downward. During the period that the slide 5843 is driven downward an ear 5849 on the lower end of the slide engages an ear 5850 on a latch restore slide 5851 which is mounted for vertical movement on shafts 5844 and 5845. The latch restore slide 5851 normally is maintained in the position shown by a frame stud 5852 which is engaged with a notch 5853. The slide 5851 is forced rightward and downward by a spring 5854 to maintain the engagement between the notch 5853 and the stud 5852. When the slide 5843 is driven downward, the ear 5849 drives the ear 5850 downward, driving the slide 5851 downward. This causes the slide 5851 to detent downward to a position in which the stud 5852 is engaged with a notch 5856. Also during downward movement of the conditioning slide 5843, an ear 5858 on the slide is driven against the lineup setting link 5803, forcing the link CCW to a position for engagement with the ear 5806 (FIG. 58) on rack 5807. When the latch restore slide 5851 (FIG. 58A) is detented downward by the ear 5849, an ear 5859 is moved downward from engagement with a tail of a division lineup latch 5861. The latch 5861 is mounted on the stud 5852 and rocked CW by a spring 5862 when the ear 5859 moves away from the tail of the latch. However, with the rack 5807 in the centralized position shown, the latch is rocked only slightly CW until a left nose 5863 is blocked by the ear 5806.

As the cam 3229 is rotated CCW during a 1st ÷ cycle, the stud 5809 first moves to the position 5809-A and drives the lever 5812 CW, forcing the surface 5810 of the link 5803 leftward against the ear 5806. The segment 5808 and shaft 5527 are driven CW thereby forcing the noses 5535 (FIG. 55), of the lineup stops 5526 which are to the left of the highest order of the dividend value (or the highest divisor value in case the dividend is smaller than the divisor), CW against respective subzero ears 5534. The springs 5530 of the stops which engage an ear are detented from the CW groove 5528 to the CCW groove 5529. The other lineup stops, which are associated with the orders in which the dividend value lies, are not detented since the racks are rightward at this time (line 5A, FIG. 5) and the subzero ears 5534, therefore, are to the right of the noses 5535.

The shaft 5527 and the lineup stops 5526 are centralized as the stud 5809 (FIG. 58) falls to the right of the shoulder 5811, just as in multiplication. Further rota-

tion of the stud 5809 brings it to the position 5809-C, against the hook 5829, for driving the lever 5812 CCW. The hook portion 5805 of the link 5803 is carried rightward into engagement with the ear 5806, driving the rack 5807 and ear 5806 rightward to the backset position 5806-BS. Since there is no shortcut carry involved in a division operation, no additional lineup stops are detented. As the ear 5806 is moved rightward to the position 5806-BS out of engagement with the upper surface of the nose 5863, the latch 5861 is rocked CW so that the nose 5863 is in a position to block leftward movement to the centralized position of the rack 5807 when the stud 5809 moves out of engagement with the hook 5828. The lever 5812 centralizes as before, but the rack 5807 cannot centralize since the ear 5806 is blocked by the latch 5863 in a division lineup position 5806-D. With the rack 5807 blocked in this position, the segment 5808 is held in a division lineup position 5808-D. The shaft 5527 is held thereby in a corresponding position. The lineup stops 5537 (FIG. 55A) with springs 5530 in the CCW groove 5529 are carried by the shaft to a division position 5526-D in the path of the pin carriage tab 5550; and the stops with springs in the CW groove 5528 are carried to a position 5526-K, clear of the tabs 5544 and 5550.

When the lineup setting link 5803 is moved rightward, as discussed earlier, an unlatching stud 5864 (FIG. 58A) on the link 5803 is brought against the latch 5846, forcing the latch CW from beneath the frame shaft 5845. This permits the spring 5848 to move the slide 5843 to the position shown with the ear 5858 away from the link 5803. The link 5803 therefore rises clear of the ear 5806 when it is centralized by the lever 5812.

P-÷ cycle.—The next cycle is a P-÷ cycle during which the countout carriage 6001 (FIGS. 55A and 60) is latched to the pin carriage 205 by means of the bail 6005 and the two carriages released for movement leftward by the springs 2612 and 6007. The carriages are latched together and released leftward near the end of a P-÷ cycle by the means discussed hereinbefore. Generally, such latching and release is in response to CW rocking of the bail 4521 (FIG. 43) from the level 4521-LU when the bail is cammed away from the surface 4328 P-÷ of the division plate 4301. Leftward movement of the carriages is stopped when the tab 5550 (FIGS. 23A and 55A) on the pin carriage engages the lineup stop 5526 to the left of the highest order dividend value. With the carriages stopped in this position, the highest order of the divisor is lined up with the highest order of the dividend. During the P-÷ cycle the links 5803 and 5820 are clear of the ear 5806 so that the rack 5807 and the shaft 5527 remain latched in the division lineup position by the latch 5861. The drive lever 5812 and links 5803 and 5820 therefore are idly reciprocated during a P-÷ cycle.

First digitization cycle.—With the division plate 4301 (FIG. 43) in the D_N position, the counter register 211 (FIG. 55) is raised for engagement with the single tooth gear 346 at the period indicated on line 54B (FIG. 54) by means discussed hereinbefore in the "Multiplier and Counter Register Controls" section. The counter register end plate 5514 is raised by CW rocking of the box cam 5511. A leftward extending shoulder 5551 on the lower end of the end plate 5514 underlies the reset pickup lever 5831 (FIG. 58). As the end plate 5514 is raised, the reset pickup link is also raised, thereby raising the lineup reset link 5820 to which the lever 5831 is pivoted. The link 5820 is raised thereby for engagement with the ear 5806 on the rack 5807. An ear 5865 (FIGS. 58 and 58A) on the end plate 5514 engages a leftward extending arm 5866 on the latch restore slide 5851 as the end plate is raised, detenting the slide 5851 from notch 5856 to notch 5853 over the frame stud 5852. The slide 5851 is moved thereby from the lower to the upper position, bringing the ear 5859 against the tail of the division lineup latch 5861 to drive the latch CCW out of engagement with the ear 5806. This permits the spring 5827 to move the

rack 5807 leftward to a position at which the ear 5806 is against the surface 5837 of the link 5820, which link is held raised by the lever 5831.

The holding and shifting racks 5845 and 6223 (FIG. 55A) are brought into engagement with the countout carriages nose 5546 when the counter register 211 is raised for engagement with the single tooth gear 346 by the following means. The follower 5513 (FIG. 55) extends beneath the digitation lever 6201 (FIG. 62) so that the lever is rocked CCW whenever the counter register is raised for engagement with the single tooth gear. Such rocking releases the holding and shifting racks 5545 and 6223, as during multiplication, for engagement with the countout carriage 6001. With the countout carriage so held, the cam 3229 (FIG. 58) drives the link 5820 rightward, forcing the ear 5806 to the backset position 5806-BS. The lineup stops 5526 in the CCW groove 5529 are detented thereby to the CW groove 5528. When the lineup reset link 5820 is driven rightward, the reset pickup lever 5831 is carried rightward therewith, away from the shoulder 5551. The lever 5831 and the link 5820 are freed thereby to rock CCW when the surface 5837 is clear of the ear 5806. When the link 5820 is driven leftward, the left face of the lever 5831 is brought against a vertical surface of the end plate shoulder 5551 thereby permitting the lineup reset link 5820 to rock CCW by the spring 5819, out of engagement with the ear 5806 when the rack 5807 is centralized. During the remaining cycles of a division operation, the links 5803 and 5820 are reciprocated idly, clear of the ear 5806, leaving the rack 5807, segment 5808, and lineup stops 5526 centralized.

SHORT-CUT SENSING AND CONTROL MECHANISM

In short-cut multiplication of the type employed in the invention, a digitation cycle is carried out additively when the controlling order of the multiplier register represents a value from 1-4 and is carried out negatively when the controlling order represents a value from 5-9. A short-cut sensing and control mechanism 6301 (FIG. 63) is provided for indicating which orders of the multiplier call for additive entry of multiplicand into the accumulator register and which orders call for subtractive entry. After being set for such indication during a multiplier entry cycle, the mechanism 6301 is used thereafter during a multiplication operation to control the program unit 229 to carry out a D_N cycle for additive entry or a D_R cycle for subtractive entry according to the indication.

The arrangement of the invention is such that during a multiplication operation, digitation is started during the second cycle of the operation, prior to any short-cut sensing of the highest order of the multiplier. Such digitation is invariably additive. As discussed hereinbefore in the "Program Unit" section and elsewhere, the first cycle of a multiplication operation is a P= cycle during which the multiplicand is printed and then lined up with the multiplier value. The mechanism 6301 takes advantage of the nature of a short-cut multiplier in that the highest order of such a value is invariably 4 or less. If the highest order of a true value is 4 or less, then the highest order of the corresponding short-cut value is the same. If the highest order of a true value is 5 or more, then the corresponding short-cut carry is entered into the next higher order so that the highest order of the short-cut value is 1. In either case, the first digitation cycle is additive and in the case of a multiplier having a shortcut carry in the highest order, only a single cycle is required to reduce the highest order to 0. With this arrangement of the invention, short-cut sensing is carried out during each digitation cycle when other sensing functions occur and no extra cycles are required for short-cut sensing.

Short-cut stops

A group of short-cut stops 6303 (FIG. 63), one stop for each order of the multiplier register, are mounted on a shaft 6305. The shaft 6305 is rocked CW during a multiplier entry cycle to set the stops to indicate whether respective orders are in short-cut form. Depression of the

multiplier entry key 110, releases the multiplier plate 2714 (FIG. 27) for movement leftward to one of three active positions to initiate a multiplier entry cycle in the manner discussed hereinbefore in the "Program Unit" section. The bail 4519 is blocked therefore against one of the surfaces 2741-X_{KB}, 2741-X_A, or 2741-X_C. With bail 4519 against either the surface 2741-X_{KB} or 2741-X_A, the powered sensing slide blocking lever ear 5105 (FIG. 51) is set to the position 5105-X_A to block the powered sensing slide in the X_A position. With the bail 4519 against the surface 2741-X_C, the ear 5105 is in the position 5105-X_C to block the powered sensing slide in the X_C position. With the powered sensing slide blocked in either one of these positions, the hook 5303 is forced into engagement with the stud 5308 so that upon movement rightward of the late slide 5301 (FIG. 53), the shaft 5136 (FIGS. 51 and 55) is rocked CCW to drive the multiplier register 209 into engagement with the racks. Counterclockwise rocking of the shaft 5136 (FIG. 63) forces a power lever 6307, which is keyed to the shaft 5136, CCW therewith. When the power lever is rocked CCW, a stud 6309 on the lever is forced against a shoulder 6311 of a latch arm 6313, driving the arm downward and to the left. A spring 6315 normally holds the shoulder 6311 in engagement with the stud 6309. The upper end of the arm 6313 is pivoted at 6317 to a centralizer disk 6319 which is keyed to the left end of the shaft 6305 on which the short-cut stops 6303 are mounted. A centralizer arm 6321 is urged CCW by a spring 6323 so that a roller 6325 on the arm 6321 is forced into a notch 6327 in the centralizer disk 6319 to urge the disk to the position shown. Counterclockwise rotation of the multiplier register control shaft 5136 forces the latch arm 6313 downward and to the left against the urging of the spring 6323 until a stud 6329 on the power lever engages the mid-portion of the latch arm 6313 and forces the shoulder 6311 out of engagement with the stud 6309. The shaft 6305 is rocked CW when the latch arm 6313 is forced downward and to the left, setting the stops 6303 to indicate a true value or short-cut value in a manner presently explained. A tail 6331 drives the roller 6325 and arm 6321 CW against the spring 6323 when the latch arm 6313 is driven downward. Upon disengagement of the stud 6309 with the shoulder 6311, the spring 6323 forces the roller 6325 back into the notch 6327, thereby rocking shaft 6305 CCW to the position shown.

On each short-cut stop 6303, a detent spring 6333 is mounted on a hub 6335 which extends from the stop. A hooked end of the spring 6333 extends through a hole 6339 in the hub into engagement with one of two axial grooves formed in the shaft 6305: a CW groove 6340 or a CCW groove 6341. Normally, the short-cut stops 6303 are in the position shown with the detent spring 6333 engaged with the CW groove 6340. A sensing stud 6342 and a roller 6343 extend from each short-cut stop 6303. The stud 6342 is for sensing the associated element 321 (FIGS. 3 and 63). The sensing stud 6342 extends rightward for engagement with the element 321 while the roller 6343 does not extend so far leftward and cannot engage the element 321. The element 321 is shown in the subzero position.

Movement rightward of the element 321 to a position corresponding to values from 0-4 brings the lower edge of the element opposite the associated sensing stud 6342. With the element 321 in the subzero position shown, the stud 6342 cannot engage the element 321 because of a notch 6345 in the element. In any position from 5-9 the element 321 is too far rightward for the stud 6342 to engage. Thus, with the element in a position from 0-4, CW rocking of the shaft 6305 forces the stud 6342 against the element, thereby detenting the spring 6333 into the CCW groove 6341. Then, as the shaft 6305 is rocked CCW by the centralizer arm 6321, the roller 6343 of each detented stop is moved to a position 6343-A.

Each short-cut stop 6303 associated with an element 321 which is either in the subzero position or a position representing a value from 5-9 is not detented when the shaft 6305 is rocked CW and is centralized therefore to the original position.

Referring to lines 5A (FIG. 5) and 54C (FIG. 54), the short-cut stops 6303 are rocked CW for setting as the late slide is moved rightward, which movement is completed after the rightward stroke of the rack assemblies 300 and before the leftward stroke. The short-cut stops are set therefore before short-cut carries are registered at the end of the leftward stroke. Any rack 303 that receives a value of 4 during the rightward stroke and which receives a short-cut carry from the next lower order at the end of the leftward stroke drives the engaged numeral wheel to 5. The short-cut stop 6303 in that order, however, is not short-cut and digitation will be carried out additively since the short-cut stop 6303 was set at the end of the rightward stroke when the rack was at 4.

After a multiplier entry cycle, the numeral wheel of the highest order of the multiplier either represents a 1 resulting from a short-cut carry from the next lower order, represents a value of 4 or less or represents a value of 5 as a result of a short-cut carry into a true value of 4 in the highest order. Since one of these possibilities is invariably the case, the highest order multiplier digit is 4 or 5 (as a result of a short-cut carry) or less. In any case short-cut digitation is never carried out during the first digitation cycle. The short-cut stop 6303 (FIG. 63) is set to the position 6343-A if the highest true value is 0-4 and remains so set even if a short-cut carry is transferred to the order. If the highest order of the true multiplier is 5 or more, the short-cut stop 6303 of that order is not detented and is returned to the original position to indicate a short-cut. A short-cut carry to the next higher order is carried out when the trip slide 3204 (FIG. 32) is unlatched (line 54D, FIG. 54) after the short-cut stops are set. Since the racks 303 and elements 321 in the orders to the left of a true multiplier are maintained at subzero during a multiplier entry cycle by nine pin sensing levers 2201 (FIG. 22) in the manner discussed hereinbefore in the "Adding Machine Keys and Mechanism" section all short-cut stops associated with these orders are rocked into notches 6345 so that all higher order stops are set to indicate a short-cut. The highest short-cut stop, therefore, may be set to either position. However, by means presently described, the first digitation cycle is always an additive cycle regardless of the position of the highest order short-cut stop.

*P=*cycle

The next steps, after a multiplier entry cycle, to initiate a multiplication operation include, generally, entry of a multiplicand in the pin carriage and then depression of one of the = keys 112, 114, 116 or both keys 114 and 116. Such depression releases either the total plate 4231 (FIG. 47) or the negative plate 4233 (FIG. 48) to the P= position to initiate a P= cycle, during which cycle the pin carriage and countout carriage are latched together and escaped leftward for alignment with the multiplier in the manner discussed hereinbefore. Near the end of the P= cycle (line 39D, FIG. 39), the program drive link 4907 (FIG. 49) drives the carrier stud 4925 and driving bail 2744 (FIG. 27) leftward in the manner discussed in the "Program Unit" section. The driving bail 2744 is moved to the left of the tooth 4726 (FIG. 47) if the total plate is the active plate or a corresponding tooth on the negative plate 4233 if that plate is the active plate. In either case, the bail 2744 engages the tooth when the program drive link 4907 is forced rightward, driving the active plate rightward therewith. The 0-step stop 4937 normally is held raised while the 1-step stop 4938 normally is held CCW in the path of the stud 4925. The stud 4925 is blocked therefore against the 1-step stop so that the active plate, e.g. the total plate 4231 (FIG. 47), is

driven from the $P=$ position to the D_N position. Since the active plate is always driven one position rightward to the D_N position near the end of the $P=$ cycle, in preparation for the first digitation cycle, the first digitation cycle is invariably additive.

The sensing plate 4235 (FIG. 45) starts movement leftward at 320° of the $P=$ cycle as indicated on line 39C (FIG. 39) and in the manner discussed hereinbefore in the "Program Unit" section to permit the sensing elements to move against respective opposite surfaces of the total plate. Since the total plate is in the D_N position, the powered sensing slide bail 4519 is blocked against the surface 4722- D_N . The blocking lever ear 5105 (FIG. 51) is rocked thereby to the $=2$ position, ready for the first digitation cycle.

First digitation cycle

At the beginning of the first digitation cycle, the powered sensing slide 5101 (FIG. 51) is driven leftward (line 54A, FIG. 54) and blocked in the $=2$ position against the ear 5105. As the slide 5101 is moved to the $=2$ position, the stud 5244 (FIG. 52A) is rocked to the position $5244=2$, driving the latch 5246 CW out of engagement with the clutch dog bail 5250 to permit the spring 5252 to rock the clutch dog bail 5250 (FIGS. 49 and 52) CW. A link 4950, which is pivoted to the bail at 4951, is driven leftward as the bail is rocked CW. A yieldable interponent 4952 is mounted on the link 4950 by means of the flattened head of a stud 4953 extending from the link. Normally, the left edge of a slot 4954 in the interponent is held against the stud 4953 by a spring 4955. A hook portion 4956 is engaged with a stud 4757 (FIGS. 49 and 49B) extending from a left arm 4959 of a digitation control bail 4958. The right end of a link 4946 is pivoted at 4960 to the arm 4959 while the left end is connected to the 0-step stop 4937. Consequently, when the bail 5250 is unlatched at the beginning of the cycle, the spring 5242 moves the link 4950 leftward, the bail 4958 CCW, the link 4946 leftward, and the 0-step stop 4937 CCW. The 0-step stop drops on the carrier stud 4925 and has no effect during the first digitation cycle since the stud 4925 was positioned near the end of the $P=$ cycle. However, since the bail 5250 remains unlatched through the remainder of the digitation cycles until the bail 5320 is rocked CCW for latching at the end of digitation, the 0-step stop is free to rock CCW in the path of the stud 4925. After the bail 5250 is unlatched the 0-step stop is under control of the bail 4958 by means described below.

During the first digitation cycle the highest order numeral wheel of the multiplier is sensed for zero at 160° (line 39E, FIG. 39), in a manner specifically discussed hereinafter. If the highest order of a short-cut multiplier value is originally greater than 1, when after such sensing the pin carriage and countout carriage remain aligned with the highest multiplier order and associated short-cut stop 6303 (FIG. 63). If, however, the highest order is originally 1, the order is reduced to zero during the first digitation cycle. Then, as a result of such sensing, the carriages are shifted rightward one order, at 225° (line 39E) by means discussed hereinafter. In either case, at 290° the multiplier numeral wheel and the short-cut stop 6303 (FIG. 63) which is associated with the controlling order is sensed at 225° indicated on line 39E by a sensing element 6347 (FIGS. 55A, 60 and 63).

The element 6347 is carried on a shaft 6349 and a stud 6351 which are mounted in the sides of the countout carriage 6001. The elements 6347 remain engaged with a sensing slide 6353 (FIGS. 60, 63, 64, 64A, 65 and 65A) throughout the extent of lateral movement of the countout carriage. The right end of the slide 6353 is guided by a frame stud 6401 (FIG. 64A) while the left end is carried by an arm 6501 (FIG. 65). A cam 6403 (FIG. 64), which is keyed to the main shaft 330, is provided for driving the slide 6353 rightward and thereby driving

the element 6347 (FIG. 63) rightward, either against the roller 6343 if the order is not short-cut or clear of the roller if the order is short-cut.

During the first digitation cycle, the multiplier register 209 (FIGS. 3 and 55) is raised for engagement with the single tooth gear 346 in the manner discussed hereinbefore in the "Multiplier and Counter Register Controls" section when the early slide 5201 (FIG. 52) is driven rightward at from 40° - 70° as indicated on line 54B (FIG. 54). The multiplier register shaft 312 (FIGS. 55 and 64) is raised thereby to a position 312-A. A link 6405 is engaged with the shaft and is driven upwards therewith. A stud 6407 extends from the link 6405 into a slot in a drive link 6409 and into a vertical guide slot (not shown) in the frame. When the multiplier register is raised, the link 6409 is raised to a position in which an ear 6411 (FIG. 64A) on the link may engage a stud 6413 extending downward from the slide 6353.

As the cam 6403 is rotated CCW, a high surface 6415 rotates CW opposite a follower 6417. The follower is rocked CCW thereby to yieldably drive the drive link 6409 rightward through a spring 6419 connected between a stud 6421 on the follower 6417 and another stud on the link 6409. The link 6409 normally is driven rightward and then leftward every machine cycle with the ear 6411 clear of the stud 6413. However, when the multiplier register is raised for engagement with the single tooth gear 346, the ear 6411 is positioned for engagement with the stud 6413 so that when the link 6409 is driven rightward, the ear is forced against the stud, driving the slide 6353 rightward. The slide 6353 carries the sensing element 6347 rightward therewith against the roller 6343 (FIG. 63) on the short-cut stop 6303 if the order represents a value of 4 or less. The sensing slide 6347 is blocked thereby from further movement rightward, causing the spring 6419 to yield as the follower is rocked fully CCW. This blocking of the sensing slide prevents the 0-step stop 4937 (FIG. 49) from being rocked CW for reasons presently discussed. Later in the cycle a second surface 6423 on the cam 6403 drives the sensing slide 6353 and sensing element 6347 rightward in the same manner as the surface 6415. Both periods in the cycle at which the cam 6403 rocks the follower 6417 are indicated on line 39E (FIG. 39). The first period at 160° is necessary for other reasons presently made clear, while the second period at 290° is significant.

A short-cut stop 6303 in an order which is short-cut is in the position shown in FIG. 63. When such a stop is sensed, the element 6347 is driven fully rightward, clear of the roller 6343. The slide 6353 is driven therefore fully rightward so that a stud 6503 (FIGS. 65 and 65A) on the left end of the sensing slide 6353 is driven against a bail 6505, rocking the bail CW (FIG. 65) about a shaft 6507. An ear 6509 on a left arm 6511 of the bail 6505 is bent leftward to underlie a similar ear 6513 that is bent rightward on a right arm 6515 of the bail 4958 (FIGS. 49 and 65). As the ears engage, the bail 4958 is rocked CW, driving the 0-step stop 4937 CW, through the link 4946, out of the path of the carrier stud 4925. As discussed earlier, the bail 4958 is released to rock CCW to a position 6513-A (FIG. 65) when the bail 5250 (FIGS. 49 and 52) is unlatched early in the first digitation cycle.

In summary, assume the case where the highest order digit of a short-cut multiplier value is 1 and is a result of a short-cut carry, the short-cut stop 6303 in that order is set to the solid position shown in FIG. 63. When the surface 6415 (FIG. 64) drives the sensing element 6347 rightward, the element 6347 is driven fully rightward, permitting the slide 6353 to also move fully rightward thereby rocking the 0-step stop 4937 (FIG. 49) CW in the manner discussed. However, since the 0-step stop was released CCW, previously, after the carrier stud 4925 was driven rightward against the 1-step stop 4938, the 0-step stop 4937 is merely rocked idly CW from a position in which the lower edge is against the carrier stud

4925. Since the highest multiplier order represents a 1, the order is counted down to 0 around 100° (line 54E, FIG. 54) of the cycle in the manner discussed hereinbefore in the "Single Tooth Gear Driving Mechanism" section. The multiplier order is sensed for 0 in a manner described in a following section at 160° at the period indicated on line 39E, FIG. 39. Since a 0 is sensed the carriages are shifted one order rightward at 225° as indicated on line 39E. After shifting into the next lower order, but still within the first digitation cycle, the surface 6423 (FIG. 64) on the cam 6403 drives the sensing slide 6353 rightward and the sensing element 6347 rightward to sense the short-cut stop 6343 in the next lower order. Referring to line 39D, the program drive link 4907 (FIG. 49) is leftward at this time, forcing the stud 4925 away from the step stops. If the sensing element 6347 is in an order which is short-cut, then the element is driven fully rightward clear of the roller 6343. Such movement rocks the 0-step stop 4937 (FIG. 49) CW, out of the path of the carrier stud 4925. When the carrier stud is driven rightward at the end of the cycle (line 39D), the stud is blocked against the 1-step stop 4938. Since the driving bail 2744 (FIG. 47) moved to the left of the tooth 4730 when the powered sensing slide drove the bail fully leftward, the bail engaged the tooth 4730 during the rightward stroke of the program drive link, driving the total plate 4231 rightward to the D_R position. In this case, therefore, the second digitation cycle is a digitation reverse cycle (D_R) during which the multiplicand is subtracted from the accumulator register in the manner discussed generally hereinbefore in the "Program Unit" section and elsewhere more specifically. During the second digitation cycle when the surface 6415 (FIG. 64) drives the sensing slide 6353 and the sensing element 6347 rightward at 160° (line 39E, the same short-cut stop is sensed which was sensed near the end of the first digitation cycle. However, the link 4907 is rightward so that the 0-step stop is idly rocked CW. If the multiplier order is not driven to 0 during the second cycle, the carriages remain aligned with the second highest multiplier order so that the 0-step stop is again rocked clear of the link 4907 when the corresponding short-cut stop 6303 is sensed at 290°. During the cycle that the second highest multiplier order is counted to 0, the carriages are shifted to the next lower order at 225° of the cycle. The surface 6423 then drives the sensing slide 6353 and sensing element 6347 rightward to sense a short-cut stop in a new order and rock the 0-step stop accordingly. If the second highest order of a short-cut multiplier value, in which the highest order is 1, is not short-cut, then during the second cycle the element 6347 is blocked against the short-cut stop 6303 so that the 0-step stop 4937 remains released CCW on the carrier stud 4925 during the period that the surface 6415 drives the sensing slide and sensing element rightward. However, after sensing for 0 and shifting, the sensing slide and sensing element are driven rightward a second time by the surface 6423. Since the roller 6343 is in the position 6343-A, the sensing element and sensing slide are prevented from moving fully rightward. This leaves the 0-step stop CCW in the path of the carrier stud 4925 so that as the stud is driven rightward by the program drive link 4907, it is blocked against the 0-step stop. The driving bail 2744, which is in engagement with the tooth 4730, drives the total plate to the D_N position so that during the second digitation cycle the multiplicand value is added into the accumulator register. If, on the other hand, the highest order value of a short-cut multiplier is 4 or less but was not the result of a short-cut carry, then the short-cut stop in the highest order is in a position with the roller 6343 in the position 6343-A. The sensing slide 6353 and sensing element 6347 are blocked from being moved fully rightward. This leaves the 0-step stop 4937 against the carrier stud 4925 to which it was released when the clutch dog 5250 was unlatched earlier in the cycle. If the highest order is greater than 1 then the order

is not counted down to 0 during the first digitation cycle and no shift occurs. If this is the case, then the 0-step stop drops CCW in the path of the stud 4925 when the program drive link moves leftward near the end of the first digitation cycle (line 39D). Since the sensing slide 6353 and sensing element 6347 are again blocked against the roller 6343 in the position 6343-A when the surface 6423 drives them rightward, the 0-step stop is not rocked CW but remains in the path of the stud 4925. Thus, as the driving bail 2744 tries to drive the tooth 4730 and the total plate 4233 rightward it is prevented by engagement of the carrier stud 4925 with the 0-step stop. The total plate, therefore, remains in the D_N position to control the calculator during the second digitation cycle during which the multiplicand is added into the accumulator register. The 0-step stop is not again raised until the carriages are shifted to a lower order which is short-cut, at which time it is rocked CW, permitting the driving bail 2744 to drive the total plate to the D_R position. From the above discussion it should be apparent that the movement of the sensing slide 6353 and sensing element 6347 rightward by the surface 6415 is redundant and harmless. Such an arrangement is a matter of convenience as presently described.

More importantly, it should be clear from the preceding discussion that during a $P=$ cycle the 0-step stop is held raised, the total plate is driven one space rightward from the $P=$ position into the D_N position, and that for subsequent D_N cycles the 0-step stop is maintained in a CCW position to block the total plate in the D_N position. In order to drive the total plate to the D_R position, it is necessary to again raise the 0-step stop so that the total plate may be driven from the D_N to the D_R position.

It should also be clear that the driving bail 2744, in engagement with the tooth 4730, holds the total plate in the D_R position during appropriate periods. When the program drive link 4907 is moved leftward, the total plate shifts to the D_N position with the holding bail 2710 against the shoulder 2728. Thus, with the 0-step stop CCW, the total plate remains in the D_N position; but with the 0-step stop CW, the total plate is driven from D_N to D_R .

The short-cut stops 6303 are restored by means described in the following section.

ZERO SENSE, SHIFT, ZERO SENSE MECHANISM

During every digitation cycle of a multiplication operation, the controlling order of the multiplier, i.e., the order that is being counted down, is sensed for zero. If the order is not at zero, multiplication continues in that order during the next cycle. If the order is at zero, the pin carriage 201 and countout carriage 6001 are shifted one order rightward to a second order and that order is sensed for zero. If the second order is at zero, then the digitation portion of the next cycle is suppressed and the carriages are again shifted; and if the second order is not at zero then digitation in that order is carried out during the next cycle. Consequently, during every multiplication digitation cycle there are two zero sensings: first zero sensing and second zero sensing. The times at which these sensings are carried out are indicated on line 39E (FIG. 39). If a zero is sensed during the first zero sensing period, the pin carriage and countout carriage are shifted one order rightward during the shift period indicated on line 39E. If the order to which the carriages are shifted represents a value of more than zero, then this condition is sensed during the second zero sensing period so that digitation is carried out during the next cycle. However, if the order to which the carriages are shifted represents a zero, this value is sensed during the second zero sensing period and the next digitation cycle is suppressed, during which cycle the accumulator register is maintained in neutral and the single tooth gear 346 is not driven. Such first sensing, possible shifting, and second sensing

occurs every digitation cycle until the multiplication operation is completed.

First zero sensing

At the beginning of a multiplication operation, the early M hook 5303 (FIG. 51) raises the multiplier register 209 (FIG. 3) for engagement with the single tooth gear 346 in the manner discussed hereinbefore in the "Multiplier and Counter Register Controls" section. The register is maintained raised throughout multiplication digitation. The multiplier register shaft 312 (FIG. 55) is raised and maintained thereby in the position 312-A (FIG. 64). The right end of the shaft 312 extends through a slot 6425 (FIG. 64) in a drive link 6427 so that when the shaft 312 is raised, the drive link 6427 is rocked CCW about a stud 6429 which extends from a right arm 6430 of a zero sensing bail 6431. The link 6427 is normally held CW by a spring 6433 so that a stud 6435 on the follower 6417 is in a wide portion of a slot 6437 in the right end of the link 6427. Normally, the stud 6435 idly reciprocates through the length of the slot. When the link 6427 is rocked CCW by the shaft 312, however, a narrow portion of the slot is engaged with the stud 6435 so that as the surfaces 6415 and 6423 of the cam 6403 drive the follower 6417, the link 6427 normally is reciprocated rightward and then leftward. The bail 6431 is yieldably connected to the link 6427 by a spring 6439 so that normally the bail 6431 is rocked CCW about the shaft 6439 when the link is driven rightward. The times that the bail 6431 is urged CCW by the cam 6403 are the first and second zero sensing periods on line 39E (FIG. 39).

A zero sensing lever 6355 (FIGS. 55A, 60 and 63) is mounted on a shaft 6349 for movement with the countout carriage frame 6001. The lever 6355 is slideably engaged with a bent edge of the zero sensing bail 6431. When the bail 6431 is rocked CCW, the zero sensing lever 6355 is rocked CCW therewith. An ear 6357 (FIGS. 55A and 63) either engages or misses a detent 5553 (FIGS. 55 and 63) which is associated with the controlling order of the multiplier register 209. Such a detent is associated with each multiplier register order and indicates whether the associated numeral wheel represents a 0 or a digit from 1-9.

The detents 5553 are pivoted on the shaft 5508 (FIG. 55) and mounted and guided between teeth and slots in a guide comb 5554. The guide comb has left and right arms which are mounted on the shaft 5508 which is guided in right and left frame slots 5509 in frame member 5507. The guide comb also has right and left ears 5555 with studs 5556 extending therefrom into engagement with slots 5557 in the frames 5507. Since the end plates 5504 carry the shaft 5508, the guide comb and detents are moved vertically with the register 209 whenever it is raised or lowered. The detents 5553 are maintained in engagement with respective numeral wheels during such movement. A spring 5558 is mounted around each detent 5553, between the comb 5554 and the detent. The spring forces the detent CCW into engagement with the teeth of the associated numeral wheel. Each numeral wheel has a mutilated tooth 5559 having a portion cut away to make space for the detent. The mutilated tooth 5559 is the 0 tooth but is shown for convenience in the 9 position. When the mutilated tooth 5559 is driven opposite the detent, the spring 5558 forces the detent into the space.

During a multiplication operation, the multiplier register 209 is raised to the position 209-A for engagement with the single tooth gear 346. The detents are raised thereby to a position 5553-A (FIG. 63), as long as the mutilated tooth is in a position from 1-9. When the mutilated tooth is moved to the 0 position, the detent rocks CCW to a position 5553-B. When the zero sensing lever 6355 (FIG. 63) is rocked CCW by the bail 6431, the ear 6357 is blocked against the detent 5553 if the mutilated tooth is in a position from 1-9, causing the

spring 6439 (FIG. 64) to yield. If the mutilated tooth is in the 0 position, however, the ear 6357 is rocked fully CCW, clear of the detent. Full CCW rocking of the zero sensing bail 6431 forces the stud 6429 (FIG. 64) against a shoulder 6600 (FIG. 66) of a slide 6601 which is mounted for rightward movement on frame shafts 6603 and 6605. As the slide 6601 is driven rightward, a lever 6607 is driven CW about the shaft 6605 by means of a stud 6609 which extends from the lever into engagement with a slot in the slide 6601. A stud 6611, extending from the lower end of the lever 6607, is driven CW thereby against a shoulder 6613 in a shift link 6615. Previously the shift link was moved from the position shown to a raised position with the shoulder 6613 in the path of stud 6611.

The shift link 6615 is raised into the path of stud 6611 at the beginning of a multiplication operation when the multiplier register 209 is raised for engagement with the single tooth gear 346. When the cam 5501 (FIG. 55) is rocked CW to raise the multiplier register, the digitation lever 6201 (FIGS. 62 and 67) is rocked CCW by the stud 5547. A stud 6701 on the left arm of the lever 6201 is forced thereby against a latch 6703, forcing the latch CCW about a shaft 6705 against a spring 6707. The latch 6703 normally holds a home order slide 6709 (FIGS. 62A and 67) in the position shown against a spring force discussed hereinafter. Counterclockwise rocking of the latch 6703 releases the home order slide 6709 for movement leftward (upward in FIG. 62A). A stud 6233 on the slide is driven leftward therewith, driving an interponent 6234 CW. The interponents drives a lever 6235 CCW (FIG. 66) about the frame shaft 6603. As the lever 6235 is rocked CCW, a stud 6617, which extends into a slot in the shift link 6615, is carried to a position 6617-A. The link 6615 is raised thereby to a position for engagement of the shoulder 6613 with the stud 6611 and is maintained raised thereby throughout multiplication digitation.

Thus, when a controlling multiplier order is reduced to zero, the bail 6431 (FIGS. 63, 64 and 66) is rocked fully CCW, driving the shift link 6615 leftward against a spring 6619. A latch 6621 is pivoted to the right end of the shift link and is rocked CW thereby out of latching position with a stud 6623 on a follower 6625. With the latch 6621 clear of the stud 6623, the follower 6625 is free to engage all portions of a shift cam 6627. The shift cam is geared to the main shaft 330 (FIG. 3) at a one-to-one ratio by means not shown so that the cam makes one complete revolution every machine cycle.

In order to maintain the latch 6621 clear of the stud 6623, the zero sensing bail 6431 is latched CCW. When the zero sensing bail 6431 is rocked fully CCW, a stud 6441 (FIG. 64) on the arm 6430 of the bail 6431 is rocked to a position 6441-A (FIG. 68), clear of a latch 6801. This permits a spring 6803 to rock the latch CCW to the left of the stud, bringing a hook portion into engagement with the stud. The zero sensing bail 6431 is latched thereby in the CCW position until shifting of the countout carriage is completed, at which time the zero sensing bail is unlatched in a manner discussed hereinafter.

When a low surface 6627-A of the cam 6627 (FIG. 66) is rotated opposite the follower 6625, the follower is latched by the latch 6621 from following the surface if a digit from 1-9 is in the controlling multiplier numeral wheel. The follower engages the surface 6627-A, however, if a 0 is in the controlling order since the latch 6621 is moved clear of the stud 6623 when the shift link 6615 is driven leftward during the first zero sensing period (line 39E, FIG. 39). If there is a digit from 1-9 in the controlling order, no shifting action occurs; however, if a 0 is in the controlling order, the follower 6625 follows the surface 6627-A and is rocked CCW (FIGS. 62 and 66) about a shaft 6236. A shift rocking arm 6237 is rocked CW thereby driving a shift bellcrank 6238 CCW (FIG. 62B). A spherical stud 6299 on the left end of the shift

rocking arm 6237 is engaged in a slot in the right end of the shift bellcrank 6238 to rock the bellcrank CCW and then CW. A forked upper end 6239 of the bellcrank is mounted around a stud 6240, which stud is fastened to a right frame member 6241. The holding rack 5545 and shifting rack 6223 are also mounted on the stud 6240 as well as a similar stud (not shown) fastened to a left frame member. The right arm 6229 and left arm (not shown) of the holding rack 5545 are mounted on the studs 6240 against a shoulder which prevents the rack from lateral movement. The shifting rack 6223, on the other hand, is mounted for lateral movement on the stud 6240 but is normally held in the position shown in FIG. 62B by a spring 6242 and the forked end 6239. The bellcrank 6238 is restrained normally from CCW rotation by the cam 6627 as discussed, when a 0 is sensed, the follower 6625 is unlatched to follow the surface 6627-A. When the surface 6627-A is opposite the follower 6625, the spring 6242 forces the shifting rack 6223 one tooth space leftward. Since the holding rack 5545 and shifting rack 6223 are rocked CW (FIG. 55A) and held in engagement with the countout carriage 6001 throughout multiplication digitation in the manner discussed hereinbefore in the "Lineup Mechanism" section, one tooth of the shifting rack ratchets over the nose 5546 on the countout carriage. As the cam 6627 continues to rotate CCW, a high portion of the cam is moved opposite the follower 6625, driving the follower CW and the forked end 6239 and shifting rack 6223 rightward. The countout carriage and pin carriage are carried rightward thereby one tooth space to align the carriages and single tooth gear 346 with the next lower multiplier order. As the countout carriage is driven rightward, the holding rack 5545 is rocked CCW (FIG. 55A) by the nose 5546 against the spring 6231. When the carriages arrive at the new position, the spring 6231 rocks the holding rack CW into re-engagement with the nose 5546. Whenever the shifting rack is ratcheted leftward, the holding rack maintains the carriages in position until the driving rack re-engages the nose 5546 to drive the carriages rightward.

When the shift rocking arm 6237 is rocked CW, to carry out shifting, an end portion 6805 (FIG. 68) is driven against a restore lever 6807 which is in a position 6807-A. The lever 6807 was rocked to the position 6807-A when a zero was sensed and the zero sensing bail 6431 was latched CCW by the latch 6801 as a result. When the lever 6807 is rocked CCW, a stud 6813, extending from the lever, drives the latch 6801 CW to release the stud 6441 from engagement with the hook portion 6805 and permit the zero sensing bail to rock CW to the normal position.

During the zero sensing period that a zero is sensed in the multiplier register, the short-cut stop 6303 (FIG. 63) in the sensed order is restored to the normal position by the zero sensing lever 6355 if the stop was previously set to the short-cut position. Since the lever 6355 is rocked fully CCW by the bail 6341 whenever a zero is sensed, a rightward extending arm 6399 is moved to the position 6399-A, driving the stop 6303 to the normal position if it was set to the short-cut position.

Second zero sensing

After a shift occurs, as described above, the order into which the countout carriage is shifted is sensed during the second zero sensing period (line 39E, FIG. 39) to determine if a 0 is in that order. This sensing is done during the same cycle that the carriages are shifted, as indicated on line 39E. Following the shifting period, the surface 6423 (FIG. 64) on the cam 6403 rocks the cam follower 6417 CCW, driving the zero sensing bail 6431 and the zero sensing lever ear 6357 (FIG. 63) CCW in the manner discussed. If the zero sensing lever ear 6357 is blocked against the detent 5553 of that order, indicating a non-zero value in that order, then the spring 6439 (FIG. 64) is extended and no shifting occurs. If the zero sensing

lever misses the detent, thereby indicating that the order is at 0, then the zero sensing lever is latched as discussed before and remains latched until it is unlatched during the shifting period in the next cycle. If a zero is sensed, then the digitation portion of the next cycle is suppressed by means discussed below.

Digitation suppression.—Gear teeth 6443 are formed on the left arm 6445 of the zero sensing bail 6431 and are engaged with a zero gear 6901 (FIG. 69) so that upon CCW rocking of the zero sensing bail 6431 during the second zero sensing period, the zero gear 6901 is rotated CW. The zero gear is keyed to the shaft 6507 to which an arm 4557 (FIG. 45A) is also keyed. When the bail 6431 is rocked CCW a stud 4559 on the arm 4557 is carried CW by the arm 4557 to permit a spring 4561 to rock the latch 4547 CCW to a position 4549-A in which the nose 4549 is to the left of the edge 4550. The sensing control plate 4235 (FIG. 45) is latched rightward thereby, since the plate is rightward during the second zero sensing period as indicated on lines 39C and 39E (FIG. 39). When rocked CCW during the second zero sensing period, the zero sensing bail 6431 is latched CCW by the latch 6801 (FIG. 68). The sensing control plate 4235 remains latched rightward thereby, throughout the digitation portion 50°-160° (line 5A, FIG. 5) of the next cycle. With the sensing control plate latched rightward, the sensing elements 4515, 4517, 4519 and 4521 are maintained in the positions shown in FIG. 45, away from the active function plate even when the cam 4539 rotates to the position shown in FIG. 45A to permit the plate to move leftward. The accumulator register is maintained in the neutral position thereby, out of engagement with the racks 303, and the single tooth gear 346 is not driven. Consequently, the racks idly reciprocate during this cycle, and since the controlling multiplier numeral wheel is at 0, the single tooth gear does not drive it further. Since the zero sensing bail 6431 was latched during the second zero sensing period of the cycle preceding the suppressed cycle, the link 6615 (FIG. 66) is still leftward, maintaining the latch 6621 clear of the stud 6623. The follower 6625 is free to follow the surface 6627-A, therefore, shifting the pin carriage and countout carriage one order rightward in the manner discussed hereinbefore. The zero sensing bail is unlatched during such shifting, in the manner previously discussed, so that the latch 4547 (FIG. 45A) is rocked CW by the spring 6439 clear of the edge 4550. This frees the sensing control plate for subsequent movement leftward when permitted by the cam 4539 to enable normal digitation cycles to be carried out.

During the first zero sensing period, the latch 4547 is rocked CCW when a zero is sensed, in the same manner as it is during the second zero sensing period. However, comparing lines 39C and 39E (FIG. 39), the sensing control plate is leftward when the first zero sensing period occurs so that the latch 4547 is rocked idly CCW against the side of the sensing control plate. During shifting, the bail 6431 is rocked CW and the latch 4547 CW, before the sensing plate is returned rightward so that the sensing control plate is not latched during the first zero sensing period even though the latch 4547 is rocked.

END OF MULTIPLICATION DIGITATION

During multiplication digitation, the pin carriage and countout carriage are shifted rightward to lineup with the next lower multiplier order when each current controlling order is reduced to 0, as discussed in preceding sections. Such digitation and rightward shifting is carried out until the carriages are lined up with the lowest multiplier order or "home" order. The multiplier numeral wheel in the home order is either at 0 or is reduced to 0 in the manner previously discussed. In either case, the digitation cycle during which a zero is sensed in the home order during the first zero sensing period (line 39E, FIG. 39) is the last multiplication digitation cycle. The home order may be either the 5th order or the 1st order, the distinction

being discussed hereinafter in other sections. In the discussion of this section, however, the 5th order is the home order, but in either case, the following functions are carried out during the last digitation cycle. The pin carriage 205 is cleared; the countout carriage 6001 and pin carriage 205 are disengaged; the shifting rack 6223 and holding rack 5545 (FIG. 62B) are driven and latched away from the countout carriage nose 5546 (FIG. 55A); the multiplier register 209 (FIG. 55) is driven to the neutral position; and the active program plate, which may be either the total plate 4231 (FIG. 47) or the negative plate 4223 (FIG. 48) is driven to either the total (T) or subtotal (S) position.

Pin carriage clearance

When the pin carriage and countout carriage are shifted into the home order at the end of multiplication, that is the fifth order, a right arm 6015 of the bail 6005 (FIG. 60) engages a hub 6017 which is mounted on the shaft 6003. The hub is spring urged leftward by spring 6019 which is mounted between the hub and the side frame 6710. As discussed hereinbefore in the "Zero Sense, Shift, Zero Sense" section, the home order sensing slide 6709 (FIGS. 67 and 62A) is released leftward during a P= cycle when the cam 5501 (FIGS. 55 and 67) is rocked CW, thereby forcing the latch 6703 out of engagement with the slide 6709. As shown best in FIG. 62A, a tab 6244 extends from the hub 6017 (FIG. 60) into a slot 6245 in the home order sensing slide 6709. A four order latch 6247 is pivoted at 6248 to the home order sensing slide and is spring urged CW by a spring 6249 between the slide and the latch. Normally, a shoulder 6250 on the latch 6247 holds the tab 6244 between the sensing slide and the latch so that the hub 6017 moves to a position 6017-A with the home order sensing slide when the slide is released leftward. When the hub 6017 is re-engaged by the right arm 6015 (FIG. 60) of the bail 6005 as the countout carriage 6001 moves to the home position, the hub is moved rightward, driving the home order sensing slide rightward to the position shown in FIG. 62A. When the home order sensing slide is moved rightward, the spring 6629 (FIG. 66) rocks the lever 6235 CW since the interponent 6234 (FIG. 62A) is released for CCW movement when the stud 6233 is moved rightward. Clockwise rocking of the lever 6235 (FIG. 66) carries the stud 6617 downward from the position 6617-A to the position shown. The stud 6617 was carried to the position 6617-A when the home order sensing slide 6709 was first released leftward at the beginning of multiplication digitation. With the stud 6617 in the position shown in FIG. 66, the shift link 6615 is lowered to the position shown with the shoulder 6613 out of the path of the stud 6611. A clear link 2536, the left end of which is carried by the stud 6617, is also lowered to the position shown with a shoulder 6630 in the path of the stud 6611.

With the clear link 2536 so positioned, sensing of a zero in the home order during the first zero sensing period (line 39E, FIG. 39) causes the zero sensing bail 6341 (FIGS. 64 and 66) to rock CCW in the manner discussed in the preceding section. The stud 6611 is driven leftward thereby against the shoulder 6630, driving the clear link 2536 leftward. Leftward movement of the clear link 2536 (FIG. 25) rocks the dog bail 2527 CCW out of engagement with the tail 2525, permitting the clutch pawl 2509 to re-engage with the ratchet 2507. A pin carriage clearance is carried out as a result of such re-engagement in the manner discussed hereinbefore in the "Adding Machine Keys and Mechanism" section.

During a first cycle of a multiplication operation, i.e. a P= cycle, the tail 2525 is carried against the bail 2527. The pawl 2509 is disengaged thereby from the ratchet 2507. The disk 2511 is centralized by the roller 2558 in the detent 2556. Pin carriage clearance is suspended thereby throughout multiplication digitation until the clear

link 2536 is driven leftward during the last digitation cycle in the manner discussed above.

Disengagement of the countout carriage with the pin carriage

When a zero is sensed during the first zero sensing period of the last digitation cycle, the pawl 2509 (FIG. 25) re-engages the ratchet 2507 to drive the clear cam 2546 CCW as well as to cause a pin carriage clearance. The cam 2546 rocks the clear cam follower 2544 CCW, which in turn drives a shiftable clear plate drive link 2548 rightward, which link is pivoted to the follower at 2562. A restore bail 2550 is pivoted to the link 2548 at 2549 so that the bail 2550 is rocked CCW when the link 2548 is driven rightward. The bail 2550 is driven thereby (FIG. 61) against an arm 6133, rocking the arm CCW. When the countout carriage is latched to the pin carriage in the manner as discussed hereinbefore in the "Lineup Mechanism" section, the member 6123 and the shaft 6003 are rocked CCW, the member being keyed to the shaft. An arm 6135, also keyed to the shaft 6003, is rocked CCW with the shaft at that time, carrying a stud 6136 from the position shown to the position 6136-A. During pin carriage clearance, therefore, when the arm 6133 is rocked CCW by the bail 2550, the upper part of the arm drives the stud 6136 from the position 6136-A to the position shown, rocking member 6123 and the shaft 6003 CW to relatch the ear 6119 with the shoulder 6121. The bail 6005 (FIGS. 60 and 55A) is rocked CW therewith, disengaging one or both of the bail teeth 6009 and 6010 from engagement with the locking comb teeth 6012. The nose 6129 is also rocked clear of the arm 6131 (FIGS. 61 and 19) thereby permitting the spring 1913 to rock the nine pin stop 1901 CW to block the leftmost nine pin 304-9. The pin carriage is disengaged thereby from the countout carriage and is maintained rightward by the nine pin stop.

When the shaft 6003 (FIGS. 55A and 61) is rocked CW, the nose 5541 on the bail 6005 is rocked to the right (FIG. 60) of the tab 5542 which extends from the cross frame member 5543 thereby latching the countout carriage in the rightward position.

Shifting and holding racks disengaged from the countout carriage

During the first digitation cycle of a multiplication operation, the multiplier register 209 (FIG. 55) is raised for engagement with the single tooth gear 346 in the manner discussed hereinbefore in the "Lineup Mechanism" section. As discussed therein the multiplier register is raised when the cam 5501 is rocked CW, driving the stud 5547 against the digitation lever 6201 (FIG. 62) to force the lever CCW. The latch lever 6209 is driven CW thereby out of engagement with the latch 6215 which normally holds the shifting rack 6223 CCW out of engagement with the countout carriage by engagement of the nose 6217 with the stud 6219. The shifting rack 6223 normally holds the holding rack 5545 CCW by engagement with the nose 6227. The shifting and holding racks remain CW and in engagement with the countout carriage throughout multiplication digitation as discussed before.

When the pin carriage is cleared during the last digitation cycle as discussed previously, the restore bail 2550 (FIGS. 25 and 68) is driven CCW. When the shifting and holding racks are raised, the latch 6215 is CW with the stud 6213 in the position 6213-A. When the bail 2550 is driven CCW a tail 6809 is driven against the stud 6213, driving the latch 6215 CCW to the original position shown in FIG. 68. During such movement the nose 6217 (FIG. 62) engages and drives the stud 6219 CCW therewith, forcing the shifting rack 6223 against the nose 6227 of the holding rack so that both racks are driven CCW to the original positions out of engagement with the countout carriage.

Zero sensing bail unlatched

When the restore bail 2250 (FIG. 68) is rocked CCW during pin carriage clearance of the last digitation cycle, the bail is rocked also against a shoulder 6811 of the restore level 6807, driving the lever CCW. A stud 6813 is driven against the latch 6801 thereby driving the latch CW out of engagement with the stud 6441, permitting the stud to rock from the latched position 6441-A to the position shown. The spring 6439 (FIG. 64) thereby restores the zero sensing bail 6431 CCW to the position shown in FIGS. 64 and 68.

Multiplier register driven to neutral

When the home order sensing slide 6709 (FIG. 62A) is moved rightward by the countout carriage 6001 and the zero sensing bail 6431 is rocked CW in the manner previously discussed, the multiplier register 209 is driven to neutral by the following means. As the home order sensing slide 5709 is driven rightward by the countout carriage 6001, a wire link 6252 connected to the left end of the slide is carried rightward with the slide. The left end of the link is attached to a lever 4962 (FIG. 49B) for driving the lever CCW when the slide 5709 is moved rightward. The right end of the lever 4962 is engaged with a flange portion extending from a shuttle 4963. The shuttle is formed with a slot 4964 which is positioned opposite a mating key 4965 which extends from an arm 4966 (FIGS. 49 and 49B). During digitation, when the home order sensing slide 6709 is leftward, the shuttle 4963 is spring urged rightward by a spring 4957 to the position shown in FIG. 49B. When the slide 6709 is moved rightward, the shuttle is driven leftward into engagement with the key 4965.

When the zero sensing bail 6431 (FIG. 64) is rocked CCW during the last digitation cycle, the gear teeth 6443 formed on the left arm 6445 (FIGS. 64 and 69) drive the zero gear 6901 CW. The gear 6901 is keyed to the shaft 6903 (FIG. 49B) so that the shaft is rocked CW when the zero sensing bail 6431 is rocked CCW. The left end of the shaft 6003 is formed with a key 4968 which always remains in engagement with a mating slot in the shuttle 4963, even when the shuttle is driven into engagement with the key 4965. Since the shuttle 4963 is engaged with the key 4965 during the last digitation cycle, the arm 4966 is rocked CW (FIG. 49) with the shaft 6903 during the first zero sensing period of the last digitation cycle.

During the first digitation cycle, the multiplier register 209 is raised for engagement with the single tooth gear 346 in the manner discussed hereinbefore in the "Multiplier and Counter Register Control" section. As discussed in that section, the latch 5246 (FIG. 52A) is driven CW to unlatch the clutch dog bail 5250 which then is rocked CW by the spring 5252 into the path of the tail 5254. When the tail 5254 rotates against the bail the clutch pawl 5210 is disengaged from the ratchet gear 5206 thereby preventing further rotation of the cam 5216 so that the early slide 5201 remains rightward. The early slide 5201 (FIG. 52) remains rightward throughout digitation until the last digitation cycle when the clutch dog bail 5250 is rocked CCW and relatched to permit re-engagement of the pawl 5210 with the ratchet gear 5206 to drive the early slide 5201 leftward. During the period that the clutch dog bail 5250 (FIGS. 52 and 49) is CW, the link 4950 is leftward so that the right edge of a slot 4969, in the left end of the link 4950, is leftward against a stud 4970 which extends from the arm 4966. When the zero sensing bail 6431 is rocked as a result of sensing a zero during the first zero sensing period of the last digitation cycle, the shaft 6903, shuttle 4963 and arm 4971 are rocked CW, driving the stud 4970 against the link 4950, to a position 4970-A. The clutch dog bail 5250 is rocked CCW thereby and relatched with the latch 5246 (FIG. 52), clear of the tail 5254. As the early slide 5201 is driven leftward, the multiplier register 209 (FIG. 55) is lowered away from the single tooth gear 346 to the

10

neutral position shown in the figure in the manner discussed before.

Since the cam 5501 (FIG. 55) is rocked CCW to lower the multiplier register 209, the digitation lever 5201 (FIGS. 62 and 67) is rocked CW by the spring 6211 (FIG. 62) as the stud 5547 is moved away from the lever. This permits the latch lever 6209 to re-engage the stud 6213 which is being held in the position shown at this time by the restore bail 2550 (FIG. 68) as discussed previously. The shifting and holding racks 6223 and 5545 are latched thereby in the CCW position after being driven CCW during the pin carriage clearance discussed previously.

Clockwise rocking of the digitation lever 6201 (FIG. 67) also moves the stud 6701 away from the latch 6703 to permit the spring 6707 to rock the latch back into engagement with the home order sensing slide 6709 (FIG. 62A), thereby maintaining the slide in the rightward home order position to which it is driven by the countout carriage 6001.

Total or negative plate driven to total or subtotal position

In order to drive the active function plate, either the total plate 4231 (FIG. 47) or the negative plate 4233 (FIG. 48), to the total (T) or subtotal (S) positions during the last digitation cycle, and 0- and 1-step stops 4937 and 4938 (FIG. 49) are maintained clear of the carrier stud 4925 by means presently described as the stud is moved rightward from 270° to 350° (line 39D, FIG. 39). With these step stops out of the way, the active function plate is driven to the total position. The active function plate, however, is driven to the subtotal position if the subtotal = key 114 is depressed to initiate multiplication instead of the total = key 112. As discussed in the "Program Unit" section, the arm 4253 (FIGS. 42 and 49) drives the 2-step stop CW, clear of the stud 4925 in response to such depression.

1-step stop rocked clear.—As previously discussed, when the shuttle 4963 is rocked CW by the zero sensing bail 6431 (FIG. 64) during the first zero sensing period (line 39E, FIG. 39) of the last digitation cycle, the lever 4966 is rocked CW therewith. An interponent 4972 is pivoted at 4973 to the arm 4966 and is urged CW about the pivot by a spring 4974 connected between the interponent and the stud 4970 on the arm. When the arm 4966 is rocked CW, an ear 4975 on the interponent is raised to a position 4975-A above a shoulder 4976 on the 1-step stop 4938. During pin carriage clearance (line 17B, FIG. 17), the arm 4966 is rocked CCW by the shuttle 4963, driving the ear 4975 downward to a position 4975-B against the shoulder 4976. The 1-step stop is driven thereby from the CCW position to the CW position shown, clear of the carrier stud 4925.

0-step stop rocked clear.—As discussed hereinbefore, the zero sensing bail 6431 (FIG. 69) is rocked CCW during the first zero sensing period (line 39E, FIG. 39) of the last digitation cycle, driving the zero gear 6901 and the shuttle 4963 (FIG. 49) CW. The shuttle drives the arm 4966 CW which in turn drives the link 4950 rightward by means of the stud 4970. As the link 4950 is moved rightward, the yieldable interponent 4952 is urged rightward through the spring 4955 connected between the interponent and the link. The hook portion 4956 of the interponent overlies the stud 4957 extending from the arm 4959 to yieldably urge the bail 4958 CW. The link 4950 and the clutch dog bail 5250 are driven and latched rightward when the zero sensing bail is rocked CCW in the manner discussed hereinbefore. The interponent 4952 continues to be urged rightward thereby after such latching. The right end of the link 4946 is connected at 4960 to the arm 4959 of the bail 4958. A slot in the left end of the link 4946 is engaged with a stud 4977 extending from an upper arm of the 0-step stop.

If, during the last multiplication digitation cycle, the active function plate is in the D_N position, the 0-step stop

75

will be in the CCW position and in engagement with the carrier stud 4925. Since the clutch dog bail 5250 and link 4950 are driven rightward during the first zero sensing period, the spring 4955 yields so that the yieldable interponent 4952 will not rock the arm 4959 CW therewith. However, later in the cycle (line 39D, FIG. 39), the carrier stud 4925 is driven leftward clear of the 0-step stop, freeing the 0-step stop to rock CW under the urging of the spring 4955.

If the active function plate is in the D_R position during the last multiplication digitation cycle, the 0-step stop will be CW and not in engagement with the carrier stud 4925. The yieldable interponent 4952 therefore will immediately rock and maintain the 0-step stop in the position shown in FIG. 49.

Both the 0- and 1-step stops 4937 and 4938 are clear therefore of the carrier stud 4925 during the last digitation cycle when the stud is returned rightward (line 39D, FIG. 39) so that the function plate may be driven to either the total or subtotal positions.

Upon return rightward of the link 4907, an ear 4979 on the hook 4909 engages the interponent 4972, driving the ear 4975 rightward out of engagement with the shoulder 4976, permitting the interponent to return to the position indicated in the figure.

Since the active function plate is positioned in either the T or S position during the last digitation cycle, the next cycle is either a total or subtotal cycle and is carried out in the manner previously discussed in the "Program Unit" section and elsewhere.

DIVISION DIGITATION

As discussed hereinbefore, the steps leading up to the digitation portion of a division operation include, first, entry of a dividend value into the accumulator register 207, such entry being made in one of several ways. A dividend value entered into the pin carriage by means of the value keys 101 can be transferred into the accumulator register in response to depression of the add key 103; or a value developed in the accumulator register from a previous multiplication, addition or subtraction operation is already in the accumulator register so that no further action is required to place the dividend. In any case, the next step after placing a dividend value in the accumulator register is entry of a divisor value into the pin carriage by depression of value keys 101. Next, a division operation is initiated by depression of the divide key 118 (FIG. 1) which releases the division plate 4301 (FIG. 43) to the 1st $\div$ position. As discussed hereinbefore in the "Program Unit" and "Lineup Mechanism" sections and elsewhere, a 1st $\div$ cycle is carried out under control of the division plate. Near the end of the 1st $\div$ cycle, the division plate is shifted to the P $\div$ position so that a P $\div$ cycle is carried out during the next cycle as discussed in the aforementioned sections.

Summarizing the conditions in those sections at the end of the P $\div$ cycle, the countout carriage is latched to the pin carriage, the carriages are leftward in a position with the highest order in the pin carriage aligned with the highest order of the dividend, the division plate 4301 is in the D_N position, the accumulator sensing slide 4515 is set to minus against the surface 4322- D_N , the bail 4519 is against the surface 4326- D_N ready to control raising the counter register 211 for engagement with the single tooth gear 346, and the bail 4521 is against the surface 4328- D_N for control of the single tooth gear 346 to rotate one revolution CCW. The machine 100 is ready therefore to go into division digitation.

Generally, during division digitation the divisor is subtracted from the dividend during successive D_N (digitation normal) cycles until an overdraft occurs. The next cycle after an overdraft is an addback or D_R (digitation reverse) cycle during which the divisor is added into the accumulator register and then the countout carriage and pin carriage are shifted a single order rightward for align-

ment with the next lower order. In each order, successive subtractions, addback and shifting to the next lower order are carried out until the carriages reach the home order. The home order during every division operation is the 1st or lowest order. A quotient is developed therefore in four additional orders, giving a larger quotient than in conventional machines.

Certain mechanisms are conditioned for division digitation during the first digitation cycle, as follows.

The counter register shaft 313 (FIG. 55) is driven upward, carrying the register 211 upward for engagement with the single tooth gear 346. The shaft 313 is driven by the early slide 5201 (FIG. 52) as the slide is driven rightward from 40° to 70° (line 54B, FIG. 54). The slide 5201 is maintained rightward throughout division digitation as discussed before. The shaft 313 extends rightward, beneath the digitation lever 6201 (FIG. 62) so that when the shaft 313 is raised, the digitation lever is rocked CCW to release the shifting and holding racks 6223 and 5545 from the position shown in FIG. 62 to move into engagement with the countout carriage in the manner discussed hereinbefore in the "Lineup Mechanism" section. Counterclockwise rocking of the digitation lever 6201 (FIG. 67) also forces the latch 6703 CCW, releasing the home order slide 6709 for movement leftward in the manner discussed hereinbefore.

Raising of the counter register shaft 313 (FIG. 68) by the early slide brings a hub 6815 which is mounted on the shaft into engagement with a tail of a bellcrank 6817. The bellcrank is engaged with a release slide 6819 and drives the slide leftward against the latch 6247 (FIGS. 62 and 62A). The latch is rocked CCW thereby, clear of the tab 6244 to permit the carriages to drive the home order slide 6709 rightward when they move into the first order at the end of division, instead of driving the slide rightward when the carriages move into the fifth order in the manner discussed hereinbefore in the "End of Multiplication Digitation" section. Digitation is therefore carried out in four lower orders during division.

Clockwise rocking of the shaft 5148 (FIGS. 51 and 56) by the early slide 5201 as the slide is moved rightward, drives an arm 5614 CW. As the arm 5614 is rocked CW, a connecting link 5615, which is pivoted to the arm, is driven rightward therewith. A stud 5616 extends from the right end of the link 5615 into engagement with a slot in the right arm of a bail 5617, driving the bail CCW when the link is moved rightward. A left arm 5619 of the bail is rocked thereby to a position 5619-A. In this position shoulder 5620 underlies an ear 5621 of a rocking yoke 5623. The rocking yoke 5623 is held in the position shown by a spring 5624 connected between a frame stud 5625 and a stud 5627 which extends from the yoke. The stud 5627 extends through the yoke and is guided for vertical movement in a frame slot 5628. At 180° of the first digitation cycle (line 17E, FIG. 17), the accumulator register 207 is lowered into engagement with the lower rack teeth 350 to carry out a subtraction in the manner discussed hereinbefore in the "Adding Machine Keys and Mechanism" and "Program Unit" sections. As discussed in those sections, the shaft 1802 (FIGS. 18 and 56) is rocked CCW to lower the accumulator register. When the shaft 1802 is rocked CCW, the box cam 1831, which is freely mounted on the shaft 1802, is cammed CCW therewith by the shaft 310. A follower 5629 extends from a link 5630 into engagement with a camming slot 5631 in the cam 1831. The left end of the link 5630 is pivoted on a frame shaft 5632. A slot in the right end of the link 5630 is engaged with a stud 5633 extending from an interponent 5635. A slot in the right end of the interponent is engaged with the stud 5627 so that as the cam 1831 is rocked CCW, the interponent 5635 is rocked CW about the stud 5627 to a position 5635-A, in the path of the stud 5602. The stud 5602 is carried by the disk 5601 which is keyed to the main shaft 330 for 360° rotation.

tion every machine cycle. Since the shaft 1802 is rocked at 180° of the first digitization cycle, the interponent 5635 is raised to the position 5635-A when the stud 5602 is in a position 5602-A. Consequently, at the beginning of the second digitization cycle, the stud 5602 is in the position shown, ready to engage the interponent 5635. During the second digitization cycle therefore, stud 5602 is driven against the interponent 5635 from 0° to 20° (line 17E, FIG. 17). If no overdraft occurred during the first digitization cycle, then the stud 5602 drives the interponent CW about the pivot 5633 as follows. Since the shoulder 5620 is beneath the ear 5621, the interponent drives the stud 5627 and yoke 5623 CCW, pivoting them about the shoulder 5620. The yoke 5623 is rocked CCW therefore at the beginning of each cycle, except the first digitization cycle, if an overdraft did not occur as described below, during the preceding cycle.

When an overdraft occurs, a carry wave results, which may last from 240° (line 5A, FIG. 5) to the end of the cycle, with an end around carry being carried as late as 0°-20° of the next cycle. As discussed before, each time the tens carry tooth 1821 (FIG. 32) passes from 0-9 or 9-0, the trip slide 3204 is forced rightward to set up the mechanism in the next higher order to register a tens carry when the assemblies 300 (FIG. 3) are returned leftward. When an overdraft occurs the higher order numeral wheels 306 of the accumulator register 207, which are normally at zero, are successively set to 9. When the carry wave reaches the highest or leftmost order, a leftmost order trip slide 5636 (FIG. 56) is driven rightward. A stud 5638 extends from the trip slide 5636 into engagement with a slot in an interponent 5639 to drive the interponent CW about the shaft 3215. The interponent is rocked thereby to a position 5639-A beneath a left ear 5640 of the yoke 5623. With the interponent 5639 in this position, the machine is conditioned so that the next cycle is an addback cycle.

Addback cycle D_R

Since the multiplier register shaft 312 (FIG. 64) is maintained in the neutral position throughout division, the zero sensing bail 6431 (FIG. 64) is not rocked during the above mentioned digitization cycle when the overdraft occurs, and therefore does not raise the 0-step stop 4937 in the manner discussed in the "Zero Sense, Shift, Zero Sense Mechanism" section. The division plate 4301 (FIG. 43) remains thereby in the D_N position at the end of that cycle and is still in the D_N position at the beginning of the addback cycle. However, when the stud 5602 (FIG. 56) is driven against the interponent 5635 at the beginning of an addback cycle during an overdraft sensing period (line 39E, FIG. 39), the division plate 4301 is released leftward to the D_R position by the following means.

When the stud 5602 is driven against the interponent 5635, the interponent is driven rightward since the yoke 5623 is held at each end from being driven downward. The right end is held by the shoulder 5620 while the left end is held by the interponent 5639 which underlies the left ear of the yoke as a result of the overdraft during the preceding cycle. The right end of a link 5642 is carried by the stud 5633 while the left end is pivoted to a lever 6905 (FIG. 69). Another link 6907 connects the lever 6905 to a lever 6909 which is mounted on the shaft 6439. Thus, when the link 5642 is driven rightward by the stud 5602, the lever 6909 is rocked CCW.

An ear 6911 on the lever 6909 (FIGS. 65 and 69) underlies a projection 6913 extending from a right arm 6915 of the bail 6505 so that upon CCW rotation of the lever 6909, the bail 6505 is rocked CW. As discussed in the "Zero Sense, Shift, Zero Sense" section, the 0-step stop 4937 (FIG. 49) is rocked CW, clear of the stud 4925 whenever the bail 6505 is rocked CW. The 0-step stop therefore is rocked clear of the stud 4925. This permits the driving bail 2744 (FIG. 43) and spring 4927 to drive the division plate 4301 rightward to the D_R position. The

sensing elements 4515, 4517, 4519 and 4521 (FIG. 43) were forced inward against respective opposite D_N surfaces of the division plate at the end of the preceding cycle. However every D_R surface is either at the same level as the corresponding D_N surface or is at a lower level. This arrangement permits the spring 4927 to move the division plate from the D_N position to the D_R position when the 0-step stop is raised. With the division plate in the D_R position, the single tooth gear bail 4521 is positioned so that the single tooth gear 346 is driven CW to subtract a count in the active numeral wheel of the counter register. The accumulator sensing slide 4515 is positioned against the surface 4322- D_R which is at the level repeat-add.

During the correction cycle, therefore, the value in the pin carriage is added back into the accumulator register and the count placed in the counter register during the overdraft cycle is subtracted. The accumulator register and counter register are restored thereby to respective conditions that existed before the overdraft occurred.

By means presently described, the follower 6625 (FIG. 66) is unlatched at the beginning of an addback cycle so that the follower can follow the cam 6627 during the shift period (line 39E, FIG. 39) of the cycle to thereby cause the carriages to shift to the next lower order in the manner discussed hereinbefore. The follower 6625 is unlatched by means of an ear 6917 (FIG. 69) on the lever 6909 which overlies the zero sensing bail 6431 and which drives the bail CCW when the link 5642 is moved rightward by the stud 5602 (FIG. 56). The stud 6429 (FIG. 66), which extends from the right arm of the zero sensing bail 6431, is forced thereby against the slide 6601, driving the stud 6611 against the link 6615 to carry the latch 6621 clear of the stud 6623. The zero sensing bail 6431 is latched by the latch 6801 (FIG. 68) until the shift period. As discussed before, the shoulder 6613 is in the path of the stud 6611 since the home order slide 6709 is leftward at this time. When the follower 6625 is rocked CCW, it follows the cam 6627 (FIG. 62) so that the pin carriage and countout carriage are shifted one order rightward as discussed hereinbefore in the "Zero Sense, Shift, Zero Sense Mechanism" section. The zero sensing bail 6431 (FIG. 68) is unlatched during the shift period by the shift rocking arm 6237 to permit the latch 6621 to relatch the follower 6625. Upon unlatching, the zero sensing bail is rocked CW, permitting the spring 4942 (FIG. 49) to rock the 0-step stop CCW. When the carrier stud 4925 is driven leftward (line 39D) the spring 4942 rocks the 0-step stop 4937 into the path of the stud so that the division plate is driven to the D_N position at the end of an addback cycle.

Subtractions (D_N cycles) continue in the new active order until an overdraft occurs, then the divisor value is added back (D_R cycle) into the accumulator register, a count is subtracted from the counter register and the carriages are shifted one order rightward. Subtraction, addback, and shifting are carried out order by order until the carriages reach the first or rightmost order position, at which time division digitization is concluded.

The last division digitization cycle is similar in many respects to the last multiplication digitization cycle as discussed in the "End of Multiplication Digitization" section. The pin carriage is cleared, the countout carriage is disengaged from the pin carriage, the shifting and holding racks are disengaged from the countout carriage, the zero sensing bail is unlatched, the counter register instead of the multiplier register is driven to neutral, and the 0- and 1-step stops rocked CW in order to drive the division plate to the PQ position. Mechanisms are conditioned for these actions, as in multiplication, when the home order slide is driven rightward by the countout carriage when it moves into the first order. The actions are initiated when the zero sensing bail 6431 is unlatched during the shift period. A primary difference between the last multiplication digitization cycle and the last division digitization cycle is that the last division digitization cycle does not involve the shifting and holding racks, the countout carriage, or the shifting and holding racks.

tion cycle is the manner in which the zero sensing bail is latched: in division the last digitation cycle is an addback cycle so that the bail is latched at the beginning of the last cycle while in the multiplication the bail is latched in the manner previously discussed.

The remaining cycles of a division operation are carried out in the manner discussed in the "Program Unit" section, the division plate being shifted one position rightward each cycle first to the PQ position and then the RM position, since the 0-step stop is latched clear of the carrier stud 4925 by the clutch dog bail 5250.

Division end around carry mechanism

In the discussion of the "Credit Control Mechanism" section, mechanisms are operated during an addition or subtraction operation to subtract a one from the lowest order of the accumulator register 207 whenever the register passes from a positive to negative value; and conversely, whenever the accumulator register passes from a negative value to a positive value, a one is added back into the lowest order. In division this same mechanism is operable when an overdraft occurs to subtract a one from the lowest order of the accumulator register and to add that one back into the register during an addback cycle. However, certain problems arise where the divisor is evenly divisible into the dividend, for example 5 divided by 5. During the addback cycle of such a division, the end around carry mechanism discussed hereinbefore is not effective to add a one back into the register. In order to ensure the addback of a one under such conditions, additional mechanism is provided to force the addition of one into the lowest order of the accumulator register each time an addback cycle is carried out.

A stud 5561 extending from the counter register box cam 5511 (FIG. 55) is rocked CW during the first division digitation cycle, as discussed hereinbefore, to raise the counter register 211 for engagement with the single tooth gear 346. With the stud 5561 (FIGS. 55 and 68) in the neutral position or a CCW position 5561-A, it underlies an extension 6821 of a link 6823 to maintain the link in the position shown in FIG. 68. When the cam 5511 is rocked CW during the first division digitation cycle, the stud 5561 is rocked CW to a position 5561-B, clear of the extension 6821. During every addback cycle, the shift rocking arm 6237 is rocked first CW and then CCW, in the manner discussed before, to cause a shift of the carriages. A stud 6825 extending from the arm 6237 normally underlies a second extension 6827 of the credit correction link 6863. When the arm 6237 is rocked CW, the stud 6825 is carried clear of the extension 6827, permitting a spring 6829 to rock the credit correction link CCW to a position in which a shoulder 6831 is to the left of the stud 6825. When the arm 6237 is rocked CCW, the stud 6825 engages the shoulder 6831 and drives the link 6863 leftward. As the link is driven leftward, a surface 6833 is driven against the stud 5561, which is in the position 5561-B at this time, camming the correction link 6863 upward and out of engagement with the stud 6825, permitting the spring 6829 to return the correction link rightward to the position shown. When the link 6863 is driven leftward, a lever 6835, which is pivoted to the right end of the link, is rocked CW, driving a nose 6837 against a stud 6839 on a lever 6841 which is keyed to the shaft 2827. The shaft 2827 (FIGS. 33 and 68) is rocked CCW thereby carrying the lever 3301 CCW (FIG. 33) from the position 3301-A. The lever 3301 is carried to the position 3301-A whenever an overdraft occurs, i.e. when the accumulator register passes from a positive value to a negative value. When the lever 3301 is moved from the position 3301-A to the original position during an addback cycle, a one is added back into the accumulator register as discussed in the aforementioned section. Thus, a one is added back into the accumulator register during every addback cycle.

Negative dividends

If an attempt is made to carry out a division operation with a negative dividend in the accumulator register, two cycles will be taken in each order, first subtract cycle 5 and then an addback cycle. Such operation will cause the machine to cycle twice in each order and a 0 to be registered in every order of the counter register. The 0's registered in the counter register will be printed on the tape as a quotient, indicating to the operation that the machine is being misoperated.

The above operation is caused by means of a blocking lever 5644 (FIG. 56) mounted on the shaft 3215. Whenever the accumulator is in a negative condition, including representing a negative dividend, the lever 3301 (FIG. 33), which is keyed to the shaft 2827, is in the position 3301-A. A lever 5646 is keyed to a leftward extending portion of the shaft 2827 and has a stud 5648 extending into engagement with a slot in the lever 5644. Whenever the lever 3301 is rocked CW to the position 3301-A as a result of a negative dividend, the shaft 2827 rocks the stud 5648 CW and the lever 5644 CCW. The lever 5644 is positioned thereby beneath the ear 5640 as long as the accumulator register remains negative. As discussed before, an addback cycle is carried out whenever both the ears 5621 and 5640 are blocked. A further requirement is that at the beginning of the cycle, the cam 1831 is CCW, keeping the interponent 5635 raised. At the end of each subtract cycle and therefore at the beginning of the next cycle the interponent is raised so that this cycle is an addback cycle. At the end of the addback cycle and the beginning of the next, the cam 1831 is CCW, keeping the interponent clear of the stud 5602 so that the next cycle is a subtract cycle. Thus, two digitation cycles are carried out in each order whenever a negative dividend is in the accumulator register and a 0 quotient is developed.

Division overrun counter

It is possible for various reasons that during a division problem, the machine 100 may take more than ten subtraction cycles in a single order, causing the single tooth gear 346 to attempt to drive a numeral wheel 309 (FIG. 55) further CW after the lug 5759 is CW against the comb 5762. This would either jam or break the gear 346 and numeral wheel 309 or associated mechanism. Such an occurrence, for example, could be a result of a late carry wave failing to rock the interponent 5639 (FIG. 56) to the position 5639-A, the lateness being due to a worn or poorly maintained machine.

To enforce an addback cycle after 10 subtraction cycles during division, the following mechanism is provided. A counter gear 5660 (FIG. 56A) is mounted on the shaft 3215. Integral with the counter gear 5660 is a stop stud 5663 (FIGS. 56A and 56B). A torsion spring 5665, mounted between stop stud 5663 and a frame member, not shown, drives stop stud 5663 against a frame stop 5667, thus establishing a "zero" position for the counter gear. The link 5615 is moved rightward at the start of division digitation as a result of raising the counter register for engagement with the single tooth gear discussed hereinbefore. A stud 5669 on the link 5615 is moved rightward thereby, permitting a holding pawl 5671 to rock CW into mesh with counter gear 5660. As digitation proceeds, cam 1831 is rocked CCW from the centralized position shown 60 and in so doing pulls a driving pawl 5673 leftward, driving the counter gear 5660 CCW. This ratchets one tooth of the counter gear over the holding pawl 5671. Cam 1831 is rocked back and forth from the CCW position to the centralized position each digitation cycle, causing the counter gear 5660 to move one tooth space each subtraction cycle.

Integral with the counter gear 5660 is a hub 5675 (FIG. 56B) with a lug 5677 so arranged on the hub that when the counter gear is moved 10 tooth spaces, lug 5677, driv-

ing through a lug 5679 on a hub 5681 which is integral with lever 5644, causes lever 5644 to rock CCW to a position 5644-A. When lever 5644 is in the position 5644-A, beneath the ear 5640 (FIG. 56), the machine is controlled to take an addback cycle as discussed before. During an addback cycle the cam 1831 is rocked CW from the centralized position. A nose 5683 on the cam drives the holding pawl 5671 out of mesh with counter gear 5660. Simultaneously, pawl 5673 is moved rightward clear of counter gear 5660. This enables torsion spring 5665 to return the counter gear to the "zero" position.

The addback cycle automatically causes a right shift of the pin carriage to the next lower order where subtraction is again carried out until the accumulator register is overdrafted or the above described mechanism simulates an overdraft.

FOUR ORDER LATCH

Normally, the driving elements 321 (FIGS. 3 and 67) which are associated with the four lower order rack assemblies 300 (FIG. 3) are latched in the subzero position by a four order latch 7000 (FIGS. 67 and 70). The latch 7000 is urged CW by a spring 7002 to block a shoulder 6711 formed in each of the four lower elements 321. Normally, the elements 321-1-4 and associated main members 301 (FIG. 3) are maintained in the subzero position by the latch while the racks 303 are moved rightward to the zero position, thus permitting a fugitive digit entered in the lowest order to carry to higher orders at all times even though the members 301 and elements 321 are blocked.

There are, however, five periods during which the four lower order racks are unlatched to permit full movement rightward: division digitation cycles during which a quotient value is developed in the four lower orders; print quotient (PQ) cycles during which the quotient values in the counter register, including the value developed in the lower orders, is printed; print remainder (RM) cycles during which the value in the accumulator register, including the value in the four lower orders, is printed as a remainder; $\times_c$ multiplier entry cycles during which a value developed in the counter register as a quotient is transferred to the multiplier register for use as a multiplier; and multiplication operations which use as a multiplier value, a value developed as a quotient in the counter register.

Division digitation

During the first division digitation cycle, the counter register 211 (FIG. 55) is raised for engagement with the single tooth gear 346 by the cams 5511 and 6700 (FIG. 67) when they are rocked CW in the manner discussed in the "Multiplier and Counter Register Controls" section. The right end plate 6713 (FIG. 67) carries the right end of the counter register shaft 313 and is forced upward by means of the stud 6704 when the cams are rocked CW. The plate 6713 is forced thereby against the four order latch 7000 (FIGS. 67 and 70), driving the latch CCW out of engagement with the four lower order elements 321-1-4. Since the counter register is maintained raised throughout division digitation, the end plate 6713 maintains the latch 7000 out of engagement with the elements 321 during this period. However, during the last division digitation cycle, the counter register is lowered to the neutral position and during the next cycle, i.e. a PQ cycle, the counter register is lowered into engagement with the teeth 352 in order that the value in the register may be transferred to the segments 311 for printing. Since the end plate 6713 is lowered out of engagement with the latch 7000 during a PQ cycle, other means described below are required during this period to maintain the latch clear of the four lower order elements 321 so that the values in these orders may be printed.

Print quotient cycle

A lever 6717 (FIG. 67) is freely mounted on the shaft 5148 and has a stud 6719 extending into engagement with the cam 6700. Consequently, as the cam 6700 is rocked CCW to lower the register 211 into engagement with the teeth 352 near the beginning of the PQ cycle, the lever 6717 is driven CCW therewith. A control arm 6721 (FIGS. 67 and 70) is pivoted at 6723 to the lever 6717 and is driven upwards against the urging of a spring 6725 when the lever is rocked CCW. As discussed before, the last division digitation cycle is carried out with the count-out carriage 6001 (FIG. 60) in the first order so that at the end of division digitation the carriage is in the first order; and by means discussed hereinafter, the countout carriage is latched in the first order and remains latched throughout the PQ and RM cycles. Whenever the count-out carriage 6001 is in the first order, a stud 6727 (FIGS. 60 and 67), which extends rightward from the carriage, is opposite a camming surface 6729 of the control arm 6721. Consequently, when the control arm 6721 is driven upwards by the lever 6717, the camming surface 6729 contacts the stud 6727 and cams the arm 6721 rightward and upward so that an upper edge 6731 is driven against the four order latch 7000. The latch 7000 is rocked CCW (FIG. 70) thereby out of engagement with the four lower order elements 321, freeing these orders for transfer of the values therein to the printing segments for printing as part of the quotient.

Print remainder cycle

During an RM cycle, the counter register is maintained in the centralized position out of engagement with the teeth 352 (FIG. 3), while the accumulator register is maintained in engagement with the racks 303. However, the four lower order racks must be maintained free for movement rightward so that the value in the four lower orders of the accumulator register is printed. Since a PQ cycle always precedes an RM cycle, provision is made to latch the lever 6717 (FIG. 67) in the CCW position when the lever is rocked thereto by the cam 6700 near the beginning of the PQ cycle.

A latching bail 6733, having right and left upper extending arms 6735 and 6737, is mounted on a shaft 6739 and normally is maintained CCW by a spring 6741 with the arm 6735 blocked by an ear 6743. The ear 6743 is formed on the lever 6717 so that as the lever is rocked CCW, the ear rides along the left edge of the arm 6735 to a position 6343-A, permitting a shoulder 6744 to rock beneath the ear 6743. The lever 6717 is maintained thereby in the CCW position, holding the control arm 6721 against the four order latch 7000. The latch is maintained thereby out of engagement with the four lower order elements 321 throughout the PQ and RM cycles. Near the end of an RM cycle, which is a last cycle, the shiftable clear plate drive link 2548 (FIGS. 25 and 67) is driven rightward as a result of a pin carriage clearance, such a clearance being carried out every last cycle in the manner discussed hereinbefore in the "Program Unit" section. As the link 2548 is moved rightward, a stud 6745 extending from the link is driven against the arm 6737. The latching bail 6733 is rocked CW thereby, forcing the shoulder 6744 from beneath the ear 6743 to permit the lever 6717 and control arm 6721 to return to the positions shown in FIG. 67. The four order latch 7000 is restored thereby by the spring 7002 for latching the four lower order elements 321.

Quotient as multiplier

It will be recalled that during an $\times_c$ multiplier entry cycle, the value in the counter register, which may be a quotient, will be used as a multiplier. When the value to be used is a quotient, the value in the counter register, including that portion of the value in the four lower orders, is transferred to the multiplier register. It is, therefore,

necessary during such an $\times_c$ multiplier entry cycle to rock the four order latch 7000 (FIG. 70) clear of the four lower order elements 321.

Since the countout carriage remains in the first order at the end of a division operation by latching means described in a following section, the carriage is in this position during an $\times_c$ multiplier entry cycle when a quotient value is transferred to the multiplier register. During either of the other two multiplier entry cycles, i.e. $\times_{KB}$ or $\times_A$ cycles, the counter register is cleared by rotation of the counter register shaft 313 (FIG. 68) in the manner discussed in the "Counter Register Clearing Mechanism" section, prior to transfer of the value to the multiplier and counter registers. As the shaft 313 is rotated at these times, a cam 6843 (FIG. 68) drives an interponent 6845 CW, which in turn rocks a lever 6847 CCW. A projection 6850 on the lever 6847 is driven thereby against a stud 6848 extending from the release slide 6819, driving the slide leftward against the latch 6247 (FIGS. 62 and 62A). The hub 6017, if maintained in the first order position 6244-A as a result of a prior division operation, is released when the latch 6247 is rocked clear of the tab 6244. Such release permits the spring 6019 (FIG. 60) to drive the hub 6017 against the countout carriage 6001, driving the carriage from the first order to the fifth order. The aforementioned countout carriage latching means releases the countout carriage for such movement by means hereinafter described whenever the counter register is cleared. During an $\times_c$ multiplier entry cycle, however, the counter register is not cleared so that the latch 6247 is not rocked and the latching means does not release the countout carriage. Therefore, if the value in the quotient register was not originally developed as a quotient, then the tab 6244 is in and remains in the fifth order during an $\times_c$ cycle; if the value was originally developed as a quotient, then the countout carriage is maintained in the first order position by latching means. The pin 6727 (FIGS. 60 and 67) is maintained therefore in the path of the camming surface 6729 of the control arm 6721 during an $\times_c$ multiplier entry cycle if the value in the counter register is a quotient value and clear of the surface if the value is not a quotient.

During an $\times_c$ multiplier entry cycle using a quotient, cam 6700 is rocked CCW to lower the counter register into engagement with the racks. The lever 6717 is rocked CCW thereby, driving the control arm 6721 upward. Since the pin 6727 is opposite the surface 6729, the control arm 6721 is cammed rightward and upward against the four order latch 7000 so that the latch is driven CCW (FIG. 70) out of engagement with the four lower order elements 321, freeing the assemblies 300 in these orders for transfer and printing of the entire quotient value.

When the cam 6700 is rocked CCW the lever 6717 is latched by the bail 6733 as before. However, a multiplier entry cycle is also a last cycle and includes a pin carriage clearance. The shiftable clear plate drive link 2548 is driven rightward therefore, unlatching the arm 6717 as before, permitting the arm 6721 to drop clear of the four order latch, and the latch to re-engage the elements 321. During a multiplication operation which uses a quotient as a multiplier, it is not necessary to free the assemblies in the four lower orders since no part of the product is developed in these orders. During such an operation, the countout carriage 6001 while in the first order, is latched to the pin carriage are released leftward, the countout carriage moving from the first order. At the end of digitation the countout carriage has been returned to the first order. The pin carriage is operated the same during all operations in that it is always returned to the fifth order. The controls for latching the countout carriage in the first order and releasing the carriage from the first order are more fully discussed in the following section.

COUNTOUT CARRIAGE HOME ORDER CONTROLS

In order to develop quotients having at least four orders, the invention is arranged with four lower orders in each register. A quotient developed in these orders may also be used as a multiplier. Such use of the four lower orders is entirely automatic. No manipulation of extra control keys or special placement of the dividend in the accumulator register is required. Some of the automatic mechanisms required to utilize the four lower orders in the above manner have been previously discussed. It may be recalled that during division digitation, the pin carriage and count out carriage are shifted rightward into the four lower orders, digitation being carried out in each order before shifting to the next lower order. The discussion in this section is directed to automatic means for latching the countout carriage in the first order and various ways of releasing it therefrom.

The automatic means for latching the countout carriage in the first order include a latch 6021 (FIG. 60) which extends from the right arm 6015 of the bail 6005. Since the bail 6005 is rocked CCW (FIGS. 55A and 68) into engagement with the locking comb 6013 during division digitation, the latch 6021 is CCW and in the position 6021-A (FIG. 68) when the countout carriage is moved from the second order into a first order. During the last digitation cycle, the bail 6005 is rocked CW out of engagement with the locking comb 6013, as discussed before in the "End of Multiplication Digitation" and "Division Digitation" sections. The latch 6021 is carried thereby into engagement with the lever 6847 (FIG. 68). The countout carriage remains latched in this manner at the end of a division operation.

If the next operation is a multiplication operation which uses a multiplier value obtained either from the keyboard or from the accumulator register, then either a $\times_{KB}$ or a $\times_A$ multiplier entry cycle is carried out prior to initiation of such multiplication. During either a $\times_{KB}$ or $\times_A$ multiplier entry cycle, the counter register is cleared in the manner discussed hereinbefore. During such clearance, the counter register shaft 313 (FIGS. 57 and 68) is driven one revolution CW. The cam 6843 is rotated CW therewith, rocking the interponent 6845 CW and the lever 6847 CCW out of engagement with the latch 6021. During such a multiplier entry cycle, therefore, the latch 6021 is disengaged from the lever 6847, permitting the spring 6007 (FIG. 60) to move the countout carriage 6001 leftward to the position shown in FIG. 60. The countout carriage is blocked from moving further leftward by engagement of the nose 5541 with the tab 5542. At the end of a $\times_{KB}$ or a $\times_A$ multiplier entry cycle therefore, the countout carriage is in the fifth order ready for a multiplication operation in the manner discussed hereinbefore.

A multiplication operation, however, may also be carried out using a quotient as a multiplier, provided a $\times_{KB}$ or $\times_A$ multiplier entry cycle is not carried out since the last division operation. If a quotient is to be used as a multiplier in a multiplication operation, then a $\times_c$ multiplier entry cycle is carried out. In this case the bail 4519 (FIG. 27) is blocked against the surface 2741- $\times_c$ so that there is no clearance of the counter register for reasons discussed hereinbefore. This leaves the latch 6021 engaged with the lever 6847. During the multiplication operation that follows a $\times_c$ cycle, the bail 6005 is latched to the comb 6013 while the countout carriage is in the first order. When the bail 6005 is rocked into engagement with the comb, the latch 6021 is rocked to the position 6021-A (FIG. 68), clear of the lever 6847. The carriages are therefore, free for movement leftward to lineup. Since there is no counter register clearance during a $\times_c$ multiplier entry cycle, the hub 6017 remains latched rightward by the latch 6247 (FIG. 62A) so that a multiplication using a quotient as a multiplier is not ended until the countout carriage is moved through the lower four orders

to the first order. During the last multiplication digitation cycle, the latch re-engages the lever 6047 when the bail 6005 is rocked CW. As long as the quotient remains in the counter register, the release slide 6819 (FIG. 68) is not driven leftward and the arm 6047 is not rocked. This leaves the hub 6017 latched rightward by the latch 6247 and the countout carriage latched rightward by the latch 6021 at the end of the multiplication operation. Consequently, multiplication operations using an old quotient as a multiplier may be carried out indefinitely, each such multiplication ending with the countout carriage latch in the first order.

If a second division problem is carried out either after a first division problem or after a multiplication operation which uses an old quotient as a multiplier, the countout carriage must first be released leftward to the fifth order position before being latched to the pin carriage. In either case, prior to the division digitation period, the counter register is cleared, releasing the countout carriage leftward in the manner discussed above. As discussed before, however, division digitation cannot end until the countout carriage is shifted into the first order. The four lower orders are kept open during division by means of the counter register shaft 313, which shaft is raised for engagement with the single tooth gear 346 throughout division digitation. When the shaft 313 is raised, the hub 6815 (FIG. 68) is driven against the bell crank 6817. The bellcrank maintains the release slide 6819 leftward against the latch 6247 (FIG. 62A) holding it clear of the tab 6244 so that the countout carriage is shifted into the first order to drive the home order sensing slide 6709 rightward to condition the machine 100 for the last digitation cycle.

ACCUMULATOR REGISTER OVERCAPACITY CONTROLS

Accumulator register overcapacity controls are provided to prevent a value which extends into the leftmost order of the accumulator register from being transferred to the multiplier register during a multiplier entry cycle. Depression of the multiplier entry key 110 (FIG. 1) under this overcapacity condition, in an attempt to transfer the value in the accumulator register to the multiplier register, initiates a cycle during which all registers are maintained out of engagement with the racks and a series of 9's are printed. Such an arrangement prevents an obvious erroneous answer from being displayed and instead provides a display which indicates to the operator that an overcapacity condition exists.

$\times_c$ multiplier entry cycle

As discussed before, every multiplier entry cycle is initiated in response to depression of the multiplier entry key 110. However, in order to carry out a $\times_c$ cycle during which the value in the accumulator register is transferred to the multiplier register, the ST= key 114 must be depressed either with the key 110 or latched down as a result of initiation of a previous multiplication operation. In either case, the ST= keystem 3539 (FIG. 27) is lowered to a position in which the ear 4143 can block the shoulder 2730. The multiplier plate 2714 is blocked by the ear in the $\times_c$ position when the multiplier entry key 110 is depressed to release the plate leftward to initiate the cycle. The ST= key is latched down and remains latched down throughout the multiplier entry cycle and is released at the end of the cycle in the manner discussed hereinbefore in the "Control Key Conditioning Mechanism" section.

Whenever the multiplier entry key or ST= key are in raised positions, the corresponding keystems 3531 and 3539 (FIG. 42) are also in the raised positions shown in FIG. 42. A blocking arm 4255 mounted on a frame stud is prevented from CCW rotation under the urging of a spring 4256 by means of the ear 4217 on the keystem 3531 and a shoulder 4258 on the keystem 3539. Only when both keystems are depressed can the blocking arm

4255 rotate CCW. Whenever an operator attempts to transfer a value in the accumulator register to the multiplier register, both keystems are depressed. A test link 4259 (FIGS. 42 and 56) is connected to the lower end 5 of the blocking arm and prevents CCW rocking of the blocking arm whenever there is no value in the leftmost accumulator register order even though the keystems 3531 and 3539 are lowered. A numeral wheel 5650 (FIG. 56) is in the leftmost order of the accumulator register and carries a blocking member 5652 with an ear 5653 extending therefrom. Normally, the wheel 5650 and ear 5653 stand in the zero position shown. When the accumulator register contains a negative value which does not extend into the leftmost order, the wheel stands in a negative zero position and the ear in a position 5653-A. Whether the numeral wheel 5650 stands in the positive or negative zero position, the ear 5653 blocks the right end of the test link 4259 from full movement rightward. However, whenever a carry is made into the leftmost order, the ear 5653 is moved clear of the test link. If an attempt is made to initiate a $\times_c$ cycle with the accumulator in this overcapacity condition, both keystems 3531 and 3539 are lowered by depression of respective keys so that the spring 4256 moves the test link fully rightward.

Since both keystems 3531 and 3539 are lowered at this time, an ear 4260 on the left end of the blocking arm is rocked CCW to a position in which it lies slightly to the left of and above the ear 4217 on the keystem 3531. In this position, the ear 4260 is in the path of the shoulder 2724 on the multiplier plate 2714. When the keystem 3531 is lowered, the ear 4217 is moved out of engagement with the shoulder 2724, releasing the multiplier plate for movement slightly leftward to a position in which it is blocked by the ear 4260. With the multiplier plate 2714 blocked in this position, the projection 2732 (FIGS. 27 and 44) lies directly beneath the shaft 4401, holding the shaft raised. With the shaft 4401 in this position, the ear 4411 is clear of the shoulder 4412, permitting the master plate 3401 to move leftward to initiate a cycle of operation in the manner discussed hereinbefore. However, with the shaft 4401 maintained raised, the interponent 4501 (FIG. 45) is maintained raised so that the ear 4423 is clear of the path of the notch 4421 on the master plate. Movement of the master plate leftward, therefore, does not unlatch the sensing control plate 4235. Since the sensing control plate is not released leftward, the sensing elements 4515, 4517, 4519 and 4521 are maintained away from the multiplier plate, all registers thereby remaining in neutral position, out of engagement with the racks. Printing is normally enabled and the rack assemblies 300 are not blocked so that the racks are driven fully rightward and a series of 9's printed to indicate to the operator that an overcapacity condition exists in the accumulator register and that the value in the accumulator register cannot be transferred to the multiplier register. At the end of the cycle, the multiplier plate and master plate are restored by the program drive link 4907 (FIG. 49) to normal latched positions in which they are shown in the manner discussed hereinbefore.

ST negative = operation

A ST negative = multiplication operation is initiated by simultaneous depression of the N= key 116 and the ST= key 114 in the manner discussed hereinbefore. It is possible, during such a multiplication operation, that a product may be developed which causes a carry into the leftmost accumulator register order, rotating the numeral wheel 5650 (FIG. 56) out of the zero position. Provision is made therefore to hold the test link 4259 away from the ear 5653 even though both of the keys 114 and 116 are depressed. This is necessary in order to leave the wheel free to rotate during a ST negative = multiplication operation. Since the keystem 3531 (FIG. 42) is latched down during the multiplier entry cycle

151

preceding a ST negative = multiplication, the ear 4217 on the keystem is away from the blocking arm 4255. The shoulder 4258 on the ST= keystem 3539 is lowered away from the blocking arm during depression of the ST= key and the N= key. In order to prevent the spring 4256 from rocking the blocking arm CCW and driving the test link 4259 rightward against the ear 5653, a stud 4262 is provided on the lower end of the N= keystem 4813. When the N= key is depressed, the stud 4262 is moved to a position opposite the blocking arm 4255. With the stud 4262 opposite the blocking arm 4255, the arm is maintained in the position shown and prevented from movement rightward. The test link 4259 is held leftward thereby, clear of the ear 5653.

ST = multiplication operation

Following a multiplier entry cycle and entry of a multiplicand, a ST= multiplication operation may be initiated by depression of the ST= key 114. The shoulder 4258 (FIG. 42) on the ST= keystem 3539 is moved thereby away from the blocking arm 4255. The keystem 3531 is latched down during the preceding multiplier entry cycle so that the ear 4217 is away from the blocking arm 4255 when the ST= key is depressed. Since the T= keystem 4714 is lowered whenever the ST= key is depressed, a stud 4268 is provided on the T= keystem 4714 in order to prevent rightward movement of the test link 4259 against the ear 5653. Such simultaneous depression is by means of the link 3557 (FIG. 36) which underlies a stud 3537 that extends from the upper end of the ST= keystem 3539. Whenever the multiplier entry key 110 is depressed, the link 3557 is moved leftward to a position in which the ear 3560 overlies a shoulder 3561 on the T= keystem 4714. Consequently, whenever the multiplier entry key 110 is latched down, depression of the ST= keystem 3539 depresses the T= keystem 4714 in the manner discussed hereinbefore. The stud 4268 on the lower end of the T= keystem 4714 drives a disabling lever 4264 CCW and the blocking arm 4255 slightly CW. The lever 4264 is mounted on a frame shaft and has a slot in the right end which is engaged with a stud 4266 that extends from the blocking arm 4255. The blocking arm 4255 is prevented from CCW rotation by this arrangement even though the ear 4217 and shoulder 4258 are away from the blocking arm. With the blocking arm 4255 CW, the test link 4259 is leftward and prevented from interference with rotation of the ear 5653 and wheel 5650 if a carry is developed in the leftmost order of the accumulator register.

KEYBOARD OVERCAPACITY CONTROLS

Keyboard overcapacity controls are provided to prevent the entry into the keyboard of a multiplicand value having a number of orders which, when added to the number of orders in the multiplier value, results in a total that exceeds the capacity of the product register, i.e. the left 14 orders of an accumulator register 207 which contains 18 orders. Generally, the capacity of the accumulator register is the number of orders in the register available for developing a product.

In a model of the invention that was constructed, 14 orders in the accumulator register to the left of the four lower orders were provided for developing products. When a value key 101 is depressed to enter a multiplicand value in the pin carriage, which entry results in a total number of orders in the multiplier and multiplicand equivalent to the capacity of the register, i.e. 14, that condition is indicated by finger pressure that is greater than normally required to depress a value key. After that value key is depressed, the keyboard is locked to prevent further depression of any of the value keys 101.

Multiplier entry cycle conditioning

During a multiplier entry cycle, the rack assemblies 300, within which the multiplier value is represented, are

152

sensed and the overcapacity controls set to correspond to the orders of the multiplier value. As discussed hereinbefore in the "Lineup Mechanism" section, the lineup shaft 5527 (FIGS. 55A and 58) and lineup stops 5526 are rocked CW, driving the stops which are to the left of the multiplier value into corresponding subzero ears 5534 (FIG. 55A). These stops are detented thereby to the CCW position, the stops within the multiplier value remaining in the CW normal position. A latch 7101 (FIG. 71) is freely mounted on a rightward extending portion 7103 of the lineup shaft 5527 (FIGS. 71 and 72) and is held CCW by a spring 7102. When the shaft 5527 is rocked CW during lineup, a hub 7201 that is pinned to the shaft portion 7103, is rocked CW therewith. A lug 7203 is driven thereby against cooperating segments 7205 that extend from a hub portion 7206 of the latch 7101. Such driving rocks the latch 7101 out of engagement with a roller 7105 that is mounted on an arm 7107. The arm 7107 is keyed to the right end of the shaft 2202. The shaft 2202 and arm 7107 are spring urged CCW by means discussed hereinafter and are rocked CCW thereby when the latch 7101 is moved clear of the roller 7105. A nose 7109 on the arm 7107 is carried by the arm either to a lower position 7109-L or an upper position 7109-U by means presently described. The nose 7109 is stopped in the lower position if the countout carriage is in the fifth order, which is the case after a $\times_{KB}$ or $\times_A$ multiplier entry cycle is carried out. However, the arm 7107 is stopped in the upper position 7109-U if the countout carriage is in the first order. This is the case after a $\times_C$ multiplier entry cycle is carried out provided that during the cycle a value originally developed as a quotient is transferred from the counter register to the multiplier register.

With the countout carriage 6001 in the fifth order, a foot 5563 (FIGS. 55A, 71 and 72) extending therefrom is in the position shown in FIG. 72, to the left of a blocking lever 7207. The lever 7207 is rotatably mounted on a frame stud 7209 and is normally held in the position shown in FIG. 72 by a spring 7211. The spring 7211 normally forces a nose 7213 of the blocking lever 7207 against a lateral surface of the nose 7109. When the latch 7101 is rocked CW to release the arm 7107, the nose 7109 rises to the lower position 7109-L against a shoulder 7215. When the countout carriage 6001 is in the first order, the foot 5563 is in a position 5563-1, in which position the foot is engaged with the blocking lever 7207, holding the lever in a CW position with the shoulder 7215 out of the path of the nose 7109. With the countout carriage in this position, unlatching of the arm 7107 by CW rotation rocking of the latch 7101 permits the arm 7107 to rise to the upper position 7109-U with the roller 7105 against the hub 7206.

Loosely keyed to the shaft 2202 (FIG. 72) in each of the machine orders is a blocking arm 7217. Only a front view of the arm in the 8th order is shown in FIG. 72. Each of the arms 7217 are spring urged CCW by a spring 7301 as best shown in a right side view of the arm in FIG. 73. Each of the springs 7301 urge the shaft 2202 and arm 7107 which is keyed thereto, CCW by means of a key 7303.

Clockwise rocking of the lineup stops 5526 (FIGS. 55 and 73) drives the shaft 5527 and portion 7103 CW, rocking the latch 7101 out of engagement with the roller 7105. The arm 7107 and blocking arms 7217 are rocked by the springs 7301 to either the lower or upper position 7109-L or 7109-U, depending upon the position of the countout carriage as discussed above. The lineup stops 5526 to the left of the multiplier values are detented by subzero ears 5534 when the stops are rocked CW. When the lineup stops are rocked CCW to the centralized position, shown in FIG. 73, the stops to the left of the multiplier value are returned to the position 5526-M with the tail 5537 in the position 5537-A. Extensions 7305 formed on the right end of each blocking arm 7217 rise to either the upper or lower positions 7305-1 or 7305-5 upon unlatching of the

arm 7107, depending on whether the countout carriage is in the 1st order or the 5th order. In either of these positions, the extensions 7305 are in the path of respective tails 5537 so that upon centralization of the lineup stops, the stops to the left of the highest order of the multiplier value drive respective extensions 7305 and blocking arms 7217 substantially to original positions while those corresponding to orders of the multiplier value remain CCW, either in upper or lower positions 7305-1 or 7305-5, depending upon the position of the countout carriage.

Multiplicand entry sensing

After a multiplier entry cycle, a multiplicand value is entered at the keyboard. Depression of a value key 101 (FIG. 1), for example key 101-5 (FIGS. 20 and 21), forces the extension 2101 against a five pin 304-5, detenting the pin downward. At the same time, the shoulder 2103 on the associated keystem is driven against the escapement shaft 2105. The shaft 2105 is carried by arms 2001 and 2002 of the escapement bail 2003 so that the shaft and bail are driven CW against the spring 2107. The lower surface of the escapement shaft 2105 engages the 9 pin driver 2109, rocking the driver CW. The nose 2111 (FIGS. 20 and 21) of the driver detents thereby the 9 pin 304-9, which pin is in the same column as the detented 5 pin. This moves the pin 304-9 clear of the 9 pin stop 1901 (FIG. 19) to permit the pin carriage to escape leftward one order.

A spring 2113 between a link 2115 and a leftward extending arm 2116 of the escapement bail 2003 raises the link whenever the escapement bail is rocked CW by depression of a value key. The lower end of the link 2115 (FIG. 73) is connected to a lever 7307 which is keyed to the left end of the shaft 2618 to yieldably rock the shaft CCW. An overcapacity gate 7311 is slideably keyed to the shaft 2618 and is mounted outside the tape pull bail 2616 (FIGS. 23 and 26). Two tape clamps 2621, each holding one end of the tape 2623 are mounted on the arm 2619. The tape is guided over rollers 2303 and is suitably connected to the pin carriage so that when the pin carriage is escaped leftward the tape is carried CCW (FIG. 23) over the rollers and the bail 2616 rightward. The bail 2616 is carried rightward thereby one order whenever the pin carriage is escaped leftward after entry of a value therein. With the pin carriage in the 4th order, before entry of any values therein, the overcapacity gate 7311 is held in the position shown in FIG. 72 with a normal sensor 7219, which extends from the gate, aligned with a nose 7313 (FIG. 73) on the 17th order blocking arm 7217 and a lower order sensor 7221 aligned with the nose 7313 on the 13th order blocking arm. The sensor 7221 is displaced four orders rightward from the sensor 7219.

The blocking arms 7217 which are to the left of the multiplier value are held substantially in the position shown in FIG. 73 with neither the sensor 7219 or the sensor 7221 blocked from CCW rotation by any nose 7313. Value keys 101 may therefore be depressed to enter the multiplicand into the pin carriage, the pin carriage being escaped one order leftward and the gate 7311 one order rightward, until one or the other of the sensors is blocked by the nose 7313 in the leftmost multiplier order when a value key is depressed. At that time, greater than normal finger pressure is required for reasons presently described.

Multiplier sensing with value in four lower orders.—As discussed hereinbefore, when the multiplier value extends into the four lower orders, the foot 5563 (FIG. 72) is not engaged with the lever 7207 so that during the multiplier entry cycle, the blocking arms 7217 within the orders of the multiplier value are set with the noses 7313 (FIG. 73) in the position 7313-N. During entry of a multiplicand after such a multiplier entry cycle, the sensor 7221 clears the nose 7313 on all blocking arms 7217, whether the blocking arm is in an order to the left of the highest multiplier order or whether the arm is within the multiplier value. The sensor 7221, therefore, cannot cause extra pressure when a value key is depressed or cause blocking of the value keys.

of the sensor 7219, while those within the multiplier value are set to block the sensor 7221.

As each multiplicand value is entered, the overcapacity gate 7311 is rocked CCW by the link 2115 (FIGS. 21 and 73) and stepped rightward one order as the pin carriage escapes leftward. As long as the sensor 7221 is opposite a blocking arm 7217 which is in an order to the left of the highest multiplier order, the gate 7311 is freely rocked CCW.

The sensor 7221, however, is eventually aligned with the highest multiplier order. The blocking arm nose 7313 in that order is in the position 7313-L and opposite the sensor 7221. Depression of a value key 101 with the overcapacity gate in this position drives the sensor 7221 against the nose 7313. This blocks the sensor from further CCW rotation and the link 2215 from further downward movement. With the link 2215 blocked, the spring 2113 (FIG. 21) is extended and a stud 2117, which extends from the arm 2116 of the escapement bail 2003 into a camming slot in the link, cams the link rightward as the key 101 is further depressed. Since the link is long and resilient, such camming motion is permissible. A trip bellcrank 2119 (FIGS. 20 and 21) is held normally CCW by a spring 2030 (FIG. 20) so that a nose 2032 is against a portion 2121 of the link 2115. When the link 2115 is cammed rightward against the spring 2030, a rightward extending arm of the trip bellcrank, which is pivoted at 2035 to a trip link 2037, is rocked CW, driving the link 2037 forward. The trip link 2037 is guided by a slot and frame stud arrangement indicated in FIG. 20 so that the link is moved forward into engagement with the ear 2005 on the escapement interlock latch 2007, rocking the latch CCW out of engagement with the ear 2021. Since the latch 2007 is mounted on the interlock bar 2011, such disengagement permits a spring 2018, which spring is connected between a stud 2041 on the interlock bar and a frame stud 2015, to move forward. During such movement, upward extending ears 2025 and 2027 on the interlock bar move beneath the arms 2001 and 2002 of the escapement bail 2003. The forward movement of the interlock bar is blocked when the rearward edge of the slot 2012 is against the frame stud 2015.

Thus, when a value key is depressed to enter a multiplicand value which completes the number of orders that may be entered without exceeding the capacity of the product register, this fact is signalled to the operator by extra pressure being required to depress the value key against the force of the spring 2030.

With the ears 2027 and 2025 of the interlock bar beneath the arms of the escapement bail, further depression of any value key is blocked by the shaft 2105 against shoulders 2103. At such a time, the number of orders that the overcapacity gate 7311 moved rightward plus the numbers of orders in the multiplier is equivalent to the capacity of the product register, i.e. 14 in the model constructed.

Normal multiplicand entry sensing.—As discussed hereinbefore, when the multiplier value does not extend into the four lower orders, the foot 5563 (FIG. 72) is not engaged with the lever 7207 so that during the multiplier entry cycle, the blocking arms 7217 within the orders of the multiplier value are set with the noses 7313 (FIG. 73) in the position 7313-N. During entry of a multiplicand after such a multiplier entry cycle, the sensor 7221 clears the nose 7313 on all blocking arms 7217, whether the blocking arm is in an order to the left of the highest multiplier order or whether the arm is within the multiplier value. The sensor 7221, therefore, cannot cause extra pressure when a value key is depressed or cause blocking of the value keys.

The sensor 7219, however, clears only the noses 7313 in the orders to the left of the highest multiplier value since the blocking arms 7217 in these orders are maintained substantially in the position shown in FIG. 73 by

respective lineup stops 5526. Entry of multiplicand value eventually shifts the overcapacity gate 7311 to a position in which the sensor 7219 is opposite the nose 7313 of the blocking arm 7217 associated with the highest order multiplier value. Depression of a value key with the gate so positioned, drives the sensor 7219 against the nose 7313. Extra pressure is required to depress this key for the reasons discussed hereinbefore and further depression of any value key is blocked in the manner discussed.

Since the sensors 7219 and 7221 are displaced from each other by four orders, the limit of the multiplicand is reached in an order four orders rightward when there is a value in the four lower orders. The total number of orders possible in the problem remains the same, the multiplier register being effectively extended rightward automatically in this case.

Blocking arm restore

The blocking arms 7217 (FIGS. 72 and 73) and the arm 7107 are restored to the positions indicated in respective figures during the first digitization cycle of a multiplication operation. During this cycle, the lineup shaft 5527 (FIGS. 58 and 72) is rocked CCW by the segment 5808 and the rack 5807 to the reset position 5808-R in the manner discussed hereinbefore in the "Lineup Mechanism" section. Since the hub 7201 is pinned to the portion 7103 of the shaft 5527, the hub is rocked CCW with the shaft, forcing the lug 7203 against the segments 7205. The hub 7206 is driven CCW thereby against the roller 7105. The arm 7107 is forced CW thereby to the position shown in FIG. 71 and latched thereto. The shaft 2202 is rocked CW therewith, rocking the blocking arms 7217 to the position shown in FIG. 73.

Interlock bar restore

A restore arm 2045 (FIG. 20) is rocked CCW and then CW every machine cycle by means of a reciprocal cam and follower (not shown), the cam being keyed to the main shaft 330. The restore link 2023 is pivoted to the left end of the restore arm 2045 and is driven forward and then rearward thereby, every machine cycle. During this movement, the ear 2021 is carried forward to permit the latch 2007 to rock CW and relatch the ear. The ear 2021, latch 2007, and bar 2011 are restored to the positions shown when the link 2023 is moved rearward. The latch 2007, however, must be free for CW rocking in order for the latch to re-engage the ear 2021 during such movement. During the first cycle of a multiplication operation, the latch 2007 is held away from the ear 2021 by means of a right finger FIG. 34 on the master plate 3401. The latch is so held until the last multiplication cycle. The master place is released to move forward as a result of depression of the T-, ST= key to initiate multiplication. The finger engages a stud 1108 on an arm keyed to the shaft 705, rocking the shaft CCW. An ear (FIGS. 11 and 34) which extends from an arm and hub 1112, which are pinned to the shaft 705, is rocked CCW with the shaft into engagement with the downward extending ear 2005 on the escapement interlock latch 2007 to hold the latch CCW throughout digitization. During the last digitization cycle of a multiplication operation the master plate is driven rightward, driving a left finger against the stud and rocking the ear to the position shown, clear of the stud 1108. This frees the escapement interlock latch to rock CW under the urging of the spring 2019 for engagement with the ear 2021 during the forward stroke of the link 2023. The latch 2007 and interlock bar 2011 are returned thereby to the non-blocking position when the restore link is driven rearward.

Second embodiment of a latching and releasing means for blocking arms

A second embodiment of a latching and releasing means for the blocking arms 7217 (FIG. 73) is shown

in FIG. 74. In this arrangement, an arm 7401, instead of arm 7107 (FIG. 71) is mounted on the shaft 2202. A rightward extending nose 7402 of the arm 7401 is of the same shape as the nose 7109 of the arm 7109 (FIG. 71) and after the arm 7401 is released CCW, in a manner presently described, the arm 7401 functions just as the arm 7109 functioned, as discussed hereinbefore. In this new latching arrangement, the arm 7401 is not released CCW until all shortcut carries are completed. By releasing the blocking arms 7217 at this time, the shortcut stops 5526 (FIG. 73) are not required to drive the blocking arms, thereby relieving any loading on respective springs 5531. Since the arm 7401 functions as the arm 7109 after unlatching, only the time and manner of unlatching are different.

Unlatching of the arm 7401 is by means of the shaft 5136 (FIGS. 51, 55 and 74) which is rocked CCW to lower the multiplier register 209 into engagement with the racks 303 and CW to raise the multiplier register for engagement with the single tooth gear 346. An arm 7403 is keyed to the shaft 5136 for rocking therewith. A link 7407 is pivoted at 7405 to the arm 7403, the pivot being moved to a position 7405-R when the multiplier register is carried into engagement with the racks and to the position 7405-S when the register is raised for engagement with the single tooth gear. A stud 7409 extends from the arm 7401 into engagement with a slot 7410 in the left end of the link 7407. An interponent 7411 is pivoted at 7413 to the link 7407 and is spring urged CCW against an ear 7414 on the link by a spring 7415. When the multiplier register is lowered into engagement with the racks during a multiplier entry cycle, the interponent is moved leftward to a position 7411-A, the interponent being cammed over an ear 7416 extending from a latch 7417, which latch is normally engaged by means of a shoulder 7418 with an ear 7419 on the arm 7401 for latching the arm in the position shown. Such camming does not unlatch the arm 7401 but does position the interponent 7411 to drive the latch 7417 CCW.

From approximately 310° to 335° of a multiplier entry cycle (line 54C, FIG. 54) the multiplier register is raised from engagement with the racks to the neutral position. The pivot 7405 is moved thereby from the position 7405-R to the centralized position shown in FIG. 74. During such movement the interponent 7411 is driven against the ear 7416, rocking the latch 7417 CCW out of engagement with the ear 7419 on the arm 7401. This permits the arm 7401 to rise to one of two positions which correspond to the positions 7109-L or 7109-U of the arm 7107 (FIG. 71). In these positions, either the stud 7409 is near the left edge of the slot 7410 or is against the edge. As a result of the unlatching, the blocking arms 7217 (FIG. 73) are permitted to rise to either the position 7305-1 or 7305-5 or are blocked against the tails 5537 of the lineup stops 5526 for the reasons and in the manner discussed hereinbefore. Thus, if a shortcut carry from the leftmost order is called for, it is not necessary to drive the corresponding extension 7305 from one of the raised positions to a lowered position by means of the lineup stop 5526 since all shortcut carries are carried out prior to the time the arm 7401 is released CCW.

During the first digitization cycle of a multiplication operation, the multiplier register is raised for engagement with the single tooth gear. The shaft 5136 is rocked CW thereby, moving the pivot from the position shown in FIG. 74 to the position 7405-S. Such rocking drives the stud 7409, by means of the link 7407 and slot 7409 CW, rocking the arm 7401 CW therewith to a position which permits the latch 7417 to relatch with the ear 7419, thereby restoring the arm 7401 and the blocking arms 7217 (FIG. 73) to the normal positions shown in the figures.

The invention claimed is:

1. In a calculating machine that performs multiplication and division under control of a program unit, the combination of:

- (a) a division plate in said program unit with a plurality of control surfaces thereon;
- (b) a multiplication plate in said program unit with a plurality of control surfaces thereon;
- (c) means for releasing one of said plates from an inactive to an active position for subsequent control of a corresponding operation;
- (d) sensing means common to said plates and normally standing clear of said plates;
- (e) means for releasing said sensing means against the control surfaces of the one of the plates standing in an active position; and
- (f) means responsive to the sensing movements of said sensing means for controlling the machine to carry out a plurality of operations according to the control surfaces sensed on that plate.

2. In a calculating machine for performing multiplier entry, positive multiplication, negative multiplication and division operations, each of said operations being under control of a program unit, the combination of:

- (a) a plurality of program plates in said program unit, a plate being provided for each of said operations;
- (b) control means selectively operable for activating one of said plates to carry out the corresponding operation;
- (c) sensing means common to all of said plates for sensing the active one of said plates; and
- (d) means responsive to said sensing means to cause the machine to carry out the operation called for by that plate.

3. In a printing calculator for carrying out a multicyclic operation involving non-arithmetic and arithmetic functions, which functions include printing the operands involved in said operation, digitation and printing the results, the combination of:

- (a) a program unit including a program plate which corresponds to said multicyclic operation;
- (b) a plurality of non-arithmetic surfaces on said plate including surfaces calling for operand printing and others calling for result printing;
- (c) a plurality of arithmetic surfaces calling for digitation;
- (d) sensing means for sensing said surfaces;
- (e) means responsive to said sensing means for controlling the machine to carry out the functions called for by the sensed surfaces;
- (f) a control key operable to position said plate with respect to said sensing means in a first one of a plurality of active positions for sensing by said sensing means;
- (g) shifting means for shifting said plate from one active position to another; and

- (h) means including said shifting means responsive to the conclusion of a function carried out under control of non-arithmetic surfaces to shift the plate to another active position for digitation control by arithmetic surfaces and at the conclusion of digitation to shift said plate to another active position for result printing under control of non-arithmetic surfaces.

4. In a calculating machine for carrying out negative and positive arithmetic operations under the control of a program unit, the combination of:

- (a) a program plate in said program unit for control of the calculating machine to carry out negative and positive types of digitation;
- (b) means for placing the machine under control of said program plate to control the machine to carry out negative digitation;
- (c) control means responsive to the completion of negative digitation to establish an indication thereof;

(d) means responsive to the indication of said completion for advancing said program plate to control the machine to carry out positive digitation; and

(e) means responsive to said control means at the conclusion of said positive digitation for changing the program unit back to the condition of control of the machine whereby negative digitation is subsequently carried out under control of the program plate.

5. In a calculating machine according to claim 4, means responsive to the conclusion of digitation in a predetermined numerical order for altering the program unit to control the machine to carry out a non-arithmetic step.

6. In a calculating machine or the like including a register set in accordance with a value entry mechanism by means of ordinal reciprocation actuator rack assemblies, said machine having an adding machine section responsive to selective depression of adding machine keys and the zero-non-zero condition of the value entry means to position said register with respect to said assemblies to carry out add, subtract, total and subtotal cycles, the combination of:

- (a) a blocking element normally positioned in response to depression of an adding machine key;
- (b) mechanism in said section responsive to depression of one of said keys, the position of said blocking element, and the condition of said value entry means to control engagement of said register with said assemblies;
- (c) a program unit comprising a plurality of program plates, each with a plurality of control surfaces for controlling engagement of the register with said assemblies during non-adding machine arithmetic operations;
- (d) means for selective releasing of one of said plates to an active position in which one of said surfaces is in a sensing position;
- (e) sensing means operable to sense the sensing position; and
- (f) means connected to said blocking element and operable by said sensing means to position the blocking element to control the engagement of the register with the assemblies at the time and in the manner called for by the sensed surface.

7. In a calculating machine according to claim 6, means for shifting the active one of said program plates to a second active position in which another one of said control surfaces is in the sensing position; and means for cyclically controlling said sensing means to automatically sense the surface in the sensing position to control the register accordingly during each cycle.

8. In a calculating machine having a base, a numeral wheel register, actuators operable under control of a value entry mechanism for driving the numeral wheels in accordance with pre-selected values, and means for ordinarily shifting the value entry mechanism and the numeral wheel register relative to each other to permit driving different successive groups of numeral wheels, the combination of:

- (a) a program unit carried in said base and operable independently of said shifting means for controlling the calculating machine to perform a predetermined sequence of operations of the actuators and the shifting means comprising:
  - (1) a plurality of program plates in said program unit, each movable from a normally disabled position to a plurality of enabled positions between successive operations of said shifting mechanism;
  - (2) a plurality of sets of control surfaces on each of said plates;
  - (3) sensing means for sensing a set of said surfaces;
  - (4) control means selectively operable for activating one of said plates by moving said plate

159

to a first control position at which a corresponding set of surfaces are opposite said sensing means;
 (5) means responsive to said sensing means to control the machine according to the sensed surfaces; and
 (6) means for moving said one plate from said first control position through a plurality of sequential positions with said sensing means determining a different operation at each of said sensed surfaces.
